ABSTRACT OF THE DISCLOSURE

A writing system utilizing coded information input means coded in accordance with any one of a plurality of first codes, and an information output means having means actuated in accordance with a second code comprising means for generating information signals in accordance with the information in said input means, a first plurality of gate means responsive to said signal generating means for producing first output signals in accordance with the first code of information signals, a second plurality of gate means responsive to said first output signals for producing second output signals in accordance with the second code, means selectively inter-connecting said first gate means and said second gate means for producing output information in said information output means representative of the information coded in the input means, and means coupling said second gate means to the information output means.

The method of programming an automatic writing system or the like for automatic completion of a form or the like comprising the steps of: dividing said form into horizontally and vertically extending lines corresponding to printing spaces of those portions of the form to be completed, preparing a first tape having a distinguishing code at each of said vertically extending lines, preparing a second tape having a distinguishing code at each of said horizontally extending lines, programming said automatic writing system to perform a particular function at each of a plurality of locations on said form, and signaling the locations of said form in said writing unit and utilizing such signals to select a particular function.

SUMMARY OF INVENTION

The inventive principles are particularly adapted for utilization in an automated writing system comprising, in the presently preferred system: a writing unit in the form of an electrically powered typewriter; an automatic information input means in the form of a reader unit for translating information from a coded information storage input means, such as a coded paper tape or the like, into coded electrical signals representative of the coded information; and a code information storage output means, in the form of a punch unit or the like, for coding a paper tape in accordance with signals generated by operation of the reader unit or the typewriter unit or both. The typewriter unit is adapted to be automatically operable by input signals received from several sources such as coded paper tape in the reader means, from a source such as signal generating means associated with the operational mechanism of the typewriter, for example an auxiliary reader system or an automatic programming system. Thus, during manual or automatic operation of the typewriter unit, coded electrical signals are generated by operation of the typewriter which may be transmitted to the punch means to code a paper tape while, at the same time, a printed page may be produced in the typewriter.

It is a general object of the present invention to provide

an improved writing system of the type described wherein data may be fed to the system by coded information input means such as a reader-paper tape input means, or a manual input means operable from the typewriter keyboard so that the input information may be utilized to form a printed page or to produce a coded information output storage means, such as another paper tape or the like.

The writing system of the present invention is adapted to be housed in a console type cabinet wherein the main mechanical operating portions of the system are placed on an upper surface thereof and the electrical control and logic systems for the reader unit, the typewriter unit, and the punch unit are housed within spaces defined by the exterior walls of the console and beneath the upper surface thereof. The electrical systems, both the logic and control systems, are of the semiconductor type to minimize the heat generated within the system, and to minimize the size and cost of the unit. The entire system may be fitted entirely within the confines of a console which is of the size of the conventional office desk.

Accordingly, it is another object of the present invention to provide a writing system which is compact in its dimensions and of low heat generating characteristics to minimize the amount of cooling necessary for efficient operation thereof.

In automatic writing systems of the type described above, there is no standard code presently being utilized in the corresponding units of the various commercially available writing systems or even in the various business machines which form the component parts of such writing systems. Since a variety of different codes are utilized, coded information available for use in the input or output means, such as found on coded paper tape utilized with a reader unit or produced by a punch unit, may or may not be compatible with other systems.

In general, typewriter unit operation is code controlled by, for example, means of a limited number of bails which are individually selectable in various combinations. The bails are arranged to be selected in various combinations to cause the desired operation of the typewriter. Each operation of the typewriter is represented by a particular selected combination of the bails and each combination of the bails is different. Thus, a code is utilized in selection of the bails for any particular typewriter operation. In any particular system, the code being utilized in the operation of the typewriter unit itself is directly related to a particular interconnection and selection arrangement utilized in operation of the typewriter. Therefore, the input signals for causing automatic operation of the typewriter must be adapted for use with a particular typewriter actuation system. Moreover, the output code from a writing unit to a punch unit is also dictated by the particular typewriter operational code selected by actuation of the keys of the keyboard and actuation of the associated bails.

It will thus be apparent that the actuation of a particular set of interposers and bails on one typewriter unit may actuate a first character whereas the actuation of that same set of interposers and bails on another typewriter unit may actuate a second character because the particular bail code utilized may vary from typewriter unit to typewriter unit. It has been the practice to utilize the code arrangement for the bails of the typewriter in producing output signals representative of typewriter operation by generating signals from actuation of the bails. Thus, the output code may vary from machine to machine. This output code from the typewriter unit is utilized to actuate the punch unit in its operation of encoding a paper tape or the like. Thus the encoding of a paper tape in any punch unit directly connected to any typewriter unit

would vary in accordance with the particular bail code of the typewriter unit.

It is desirable that coded information storage means produced by any writing system and encoded in accordance with any particular code be adapted to be utilized interchangeably with any other particular writing system. Accordingly, it is desirable that the code punched into a paper tape may be made compatible with any writing system with which it is associated. For example, when the letter "a" is coded in a particular paper tape by one writing system, it is desired that the letter "a" be imprinted on a page in the typewriter unit of another writing system through the proper actuation of a particular code of interposers. On the other hand, the code being utilized in coding the output paper tape in the first system may or may not be compatible with the second writing system depending on the particular codes utilized.

It has been found that the interconnection between the output signals of the reader logic circuitry and the input to the typewriter logic circuitry may be made variable to insure that the paper tape being passed through the reader unit is compatible with the particular typewriter unit being utilized. Similarly, if a paper tape being produced in the punch unit is to be used in the reader unit of another system, the interconnections between the output logic circuitry of the typewriter unit and the input logic circuitry to the punch unit be made variable to accommodate the difference in codes between the typewriter unit producing the code in the punch unit and the typewriter unit which is going to utilize the paper tape produced thereby.

In this regard, it has been found that the interconnections of certain logic systems is facilitated by designating the output signal from one system and the input signal to the next system by the decimal equivalent of the binary codes. Thus an output hub from any logic system may be designated by a single decimal number which is equivalent to the particular binary code of any number of bits of information. An eight bit system may be designated by a decimal number from decimal zero to two hundred fifty-five and the user may readily determine the binary representation of the output signal by merely observing the decimal designation thereof. Similarly, an input hub may be designated in accordance with its decimal equivalent of the binary configuration of the output signal being produced at the output terminals. Thus, if an output signal in the punch unit is to be identified, the punch unit being of the eight channel configuration, for example, the input terminal to the punch unit may be designated in accordance with the decimal equivalent of the binary output. In this way, the user may readily ascertain the binary configuration of the binary output signal by observing the decimal equivalent identified with the particular input hub.

Accordingly, it is another general object of the present invention to provide a writing system having means for programming the interconnections of various components of the system to provide compatibility between any of a plurality of codes being utilized therein.

It is another object of the present invention to provide means for programming the interconnections between the output logic of a reader means and the input logic of a typewriter unit.

It is still another object of the present invention to provide means for programming the interconnections in a writing system between the output logic of the typewriter unit and the output logic of the punch unit.

It is still a further object of the present invention to provide a coded designation for the various signals in a writing system which facilitates the ascertaining of the binary code of that particular signal.

It is still another object of the present invention to provide a coded designation for various signals within a writing system to facilitate the interconnection between various portions of the electrical circuitry thereto.

In carrying out certain of the principles of the present invention, the coded output signals generated in the reader means are fed to a plurality of input storage means, in the form of a plurality of bistable devices such as flip-flop units, through a program board wherein the information being generated in the reader unit sets the conditions of the bistable devices. The outputs of the bistable storage devices are fed to an input logic circuit and, at a particular point in the cyclical operation of the system, the signals are passed to the next stage of the logic circuitry. The second stage of logic transforms the output signals to a combination of 64 output signals of which 44 are utilized in representing the various characters of the machine. The remaining 20 signals are either utilized in actuating certain machine functions in the writing system or are deleted by proper circuitry in the system. Thus, the various combinations of the input flip-flops are transformed into 64 output signals which are generated in accordance with the particular code of the information storage input means utilized in the reader unit.

A portion of the remainder of the 64 output signals, after the 44 character signals have been selected, are utilized to provide input signals to the typewriter function section to perform the various functions of the typewriter such as carriage return, index, space, back space and the like, and to perform certain system functions, such as punch on, reader on, tape skip and the like. The 44 output signals from the reader logic section are transformed, through proper logic, to a plurality of 6 output signals which are in turn fed to the typewriter interposer solenoids of the typewriter unit. These typewriter solenoids are adapted to actuate the interposer portions of the typewriter to thereby manipulate the typing mechanism of the typewriter.

The control of the operation of the logic circuit described above is maintained by a reader control circuit which is adapted to generate a strobe signal for the logic circuits and also a reset signal to reset the bistable portions of the circuit described above. The reader control circuit also provides output signals to advance the reader clutch in synchronism with the operation of the typewriter unit. In order to maintain this synchronism of the strobe, reset and reader clutch signals, a plurality of cycling signals are generated in the typewriter unit itself to signal the end of the function being performed or the advancement of the print shaft, and the reader unit generates certain other signals which are synchronized with the signals of the typewriter unit. These signals are impressed on the reader control circuit to govern the cyclical operation of the circuit. Certain other signals are generated in the punch portion of the circuit to control the operation of the reader control circuit in the situation wherein the typewriter unit itself is not being used to produce a printed page but an output tape is being punched to reproduce the coded information contained in the input tape. Thus the total operation on the typewriter unit and the reader unit are controlled through the reader control circuit.

The operations of the typewriter unit, both the character printing operation and the function operation, are sensed by signal producing means in the form of a reluctance pickup unit. This is a presently preferred method of generating an output signal which is indicative of the character being printed or the machine function being performed. These output signals from the typewriter unit are fed to the punch unit through a punch program board and the output signals are coded into a plurality of punch signals by means of a punch output logic circuit. Thus, for example, the outputs of the six bails of the typewriter unit are transformed into a plurality of eight punch signals to an eight channel punch unit through a logic circuit including a typewriter output logic system and a punch output logic system. As in the case of the reader and typewriter unit, the above mentioned logic systems are interconnected through a punch program board, the

interconnection being more fully explained hereinafter.

The operation of the typewriter output logic circuit and the punch output logic circuit is maintained in synchronism with the remainder of the writing system by means of a punch control circuit, which is closely analogous to the reader control circuit described above. The primary function of the punch control circuit is to generate a pair of strobe signals for the typewriter logic circuit and the punch logic circuit to provide a sequence of passage of information from one to the other. Also, a punch clutch output signal is generated in the punch control circuit in addition to a reset signal for various bistable means including the typewriter output logic circuits and the punch output logic circuit.

The output signal code from the punch logic section is checked by a parity check circuit wherein the parity of the particular code chosen for the punch unit is checked for odd or even parity. This check is made prior to the output signals being fed to the punch coils, thereby precluding erroneous information from being punched in the coded output storage means. Also the parity check circuit allows the information to be eliminated from the system by merely resetting the bistable information storage means through proper resetting circuit. As a further feature, the parity check circuit causes a signal to be generated which locks the typewriter keyboard to preclude an operator from manually inputting information into the typewriter unit.

Accordingly, it is another object of the present invention to provide an improved writing system which permits the use of various forms of input information, such as coded tape or cards, manual operations and the like, to derive output reproductions of the input information in the form of coded tapes or cards, a printed page or the like.

It is still another object of the present invention to provide an improved writing system having a facility wherein the form of the output information may be simply and easily selected, either automatically or manually.

It is still another object of the present invention to provide an improved writing system wherein the interconnections between various sub-systems within the writing system are greatly simplified and facilitated.

It is still a further object of the present invention to provide an improved writing system wherein the operation of the entire system is controlled and synchronized automatically, thereby adapting the writing system to various operations and functions of varying speeds.

Referring now to the specific details of the particular electrical systems of the writing system and particularly to the reader input logic circuit, the input signals from the reader unit are fed to a plurality of bistable information storage devices wherein one storage device is provided for each channel. In a preferred embodiment of the present invention, the bistable information storage devices are representatively illustrated as flip flop units wherein the signals generated in the reader unit are fed to one side thereof to switch the condition of the flip-flop units to a set condition. Also, provision has been made to reset the flip-flops at a proper point in the sequence of operation of the system. The outputs of the flip-flop units, both from the set and reset sides, are fed in various combinations to a plurality of reader input logic devices, in the form of norgates, which have been interconnected into three distinct groups thereof.

The first group corresponds to the first three channels of the reader unit or the one, two and three bit portions of the information signals, the second group corresponds to channels four, five and six or the fourth, fifth and sixth bits of information, and the third group corresponds to channels seven and eight or the seventh and eighth bits of information. The outputs of each of the sections are fed to a plurality of intermediate reader input gates wherein each input gate receives one signal from one output ter-

5 minal in each of the three bit sections described above. Thus, each input terminal will receive an input signal from the first, second and third bit sections in accordance with a particular scheme of common groups of bits.

The output signals of the flip-flop units are also fed to a plurality of auxiliary reader output logic devices which are directly connected to the punch output logic circuit. These latter gates are utilized in the nonprint mode of the writing system wherein it is desired to provide an output to the punch unit and punch a tape or other information storage device while eliminating a printed page. These auxiliary output gates are controlled in operation by certain control signals from the reader control circuit and other circuits of the system.

10 Referring back to the three groups of output gates, it is to be noted that the output signals are not passed through these gates until such time as a strobe signal is received from the reader control circuit. This strobe signal is synchronized with the operation of the reader unit to insure that all the required information has been fed to the gates and further insures that all of the information is read simultaneously. In this way the possibility of spurious signals entering the system is greatly reduced. The input signals are fed to the bistable flip flop units 15 and stored therein and this information is continuously fed to the gates until such time as the flip flop units are reset. Thus, an input signal is provided to the gates connected to the flip flop units without providing an output signal until such time as the strobe signal is impressed on the input terminals of each one of the gates.

20 The last mentioned gates are connected to a plurality of forty-four output gates of the reader logic, the output gates being grouped in accordance with a program of greatest common bits. For example in typewriter input logic, four gates are grouped in accordance with a common input denominator of signals in typewriter input channels one, two, three and four, whereas the next four gates are grouped in accordance with signals in typewriter input channels two, three and four. Each gate of 25 the group of four gates signal the various input combinations of channels five and six, as for example, only channel five, only channel six, channels five and six, and neither of channels five and six. Thus each set of four output conductors from these latter gates are grouped 30 in accordance with a particular configuration of input signals and may be fed to a single gate to provide an output in each of the channels corresponding to the common denominator channels.

35 These common denominator channels are characteristics 40 of channels one through four and the output configuration of the output gates in the typewriter input logic are accordingly interconnected with the typewriter input channels. The outputs of each of these gates are also interconnected with a second set of gates which are responsive 45 to signals in channels five and six. These latter gates provide actuating signals for input channels five and six for each group of gates having common denominator bits. In this way a minimum amount of electrical components are utilized to provide outputs to all six interposer units. While the above system has been described 50 with reference to a six channel code, it is to be understood that an eight channel code may be utilized in the input reader, in which case, the logic system is expanded to accommodate the additional channels.

55 The foregoing system of dividing the reader logic input gates into three groups, in addition to minimizing the number of electrical components in the system, further allows the system to be extended to its full capacity of eight channels in systems where an eight channel code is particularly adaptable. However, in the situation where the system is being utilized to control a typewriter unit having only forty-four characters and approximately sixteen machine function codes, it is not necessary that the full eight channels be utilized inasmuch as less than 60 sixty-four character and function codes are required to 75

completely operate the typewriter machine. With sixty-four usable codes, it is only necessary that the first six channels be punched and, accordingly, channels seven and eight may or may not be utilized. In this situation all of the output gates in the reader logic circuit would be provided with an input from the not seven and not eight section of the channel seven and eight bit section. However, as stated above, a total of eight channels may be utilized and the logic circuit interconnections would accordingly be changed. Also, the logic circuitry receiving the eight bit code would be expanded.

Accordingly, it is another object of the present invention to provide an improved reader input logic system.

It is still another object of the present invention to provide an improved logic system utilizing a preselected number of input information bits which may readily be expanded to a system utilizing a larger number of input information bits.

It is still another object of the present invention to provide a writing system having a reader logic circuit wherein an information storage device provides an output to an auxiliary output logic circuit for the transmission directly to an auxiliary output unit and thus by-passing the typewriter unit.

It is still a further object of the present invention to provide an improved logic system wherein the logic is interconnected in accordance with a program of grouped logic devices, the devices being grouped in accordance with a largest common information bit configuration.

It is still a further object of the present invention to provide an output logic system wherein the grouped devices described above are coded with identical signals for a portion of the reader channels and wherein signals are fed from the output conductors of the devices to a second group of devices to provide an output corresponding to a certain other portion of the channels.

It is still a further object of the present invention to provide a logic system wherein certain of the logic units are grouped in accordance with a maximum information bit configuration. In this configuration, each of the units within the group differ one from the other, in an additional information bit from one or more channels of the reader unit.

As stated above, each of the reader output gates of the reader input logic circuit are grouped in accordance with a maximum common information bit configuration. For example, a first group may consist of signals which are common to a sensing in channels one to four whereas a second group of four gate units are common in a factor of information bits in channels two, three and four. Accordingly, each of the output signals from the groups may be fed to a single gate, the output of which is distributed to a plurality of interposer coils in accordance with the common information bit factor. As an example, in the first case the output signals of the gate would be connected to actuate interposers one, two, three and four. Each of the gates within any one group differ, one from the other, in a designation in either channels five or six of both channels five and six or neither channels five and six.

Accordingly, the output conductor from the reader output gates are also connected to a second group of gates which are designated by a connection to interposers five and six, just interposer six or just interposer five. A final group of four gates which are solely indicative of signals in channels five and six, channel five, channel six or neither channels five and six, are fed directly to the interposer five and six gates and thus control these interposers. The plurality of interposer output gates are connected through a plurality of inverter gates to the driver circuits which are in controlling relation to the six interposers of the typewriter unit.

Thus, when a signal is received at the input to the inverter gate, the corresponding interposer will be actuated in accordance with a particular code which is character-

istic of the typewriter unit being utilized. Also, each of the outputs of the interposer gates are fed to a second driver gate which is in controlling relation to the typewriter clutch unit and, when any of the interposers have been actuated or in the situation when none have been actuated but the reader unit has advanced one step in reading the tape, the typewriter clutch will be actuated to transmit the information stored in the interposer units to the typewriter unit mechanism. In this manner, the typewriter imprinting or carriage mechanism, will type the corresponding character coded in the interposer units.

Also, the interposer output gates are provided with an inhibit signal on the inputs thereof to inhibit the output signals to the interposers in the situation where the system is in the nonprint mode. This inhibit signal is generated in the typewriter function circuit to which the nonprint signal from the reader unit is fed. In this mode, the nonprint gates in the reader input logic section are being utilized to transmit information directly to the punch unit, thus bypassing the typewriter unit. The signals being read and stored in the reader logic section are inhibited from being transmitted from the typewriter logic section to the interposer units.

Accordingly, it is another object of the present invention to provide an improved typewriter logic system wherein the typewriter operates with increased reliability and wherein the utilization of the electrical components thereof is maximized.

It is still a further object of the present invention to provide a typewriter input logic system wherein the input logic units are organized in a first group to control a portion of the typewriter input interposers and a second group of logic units are programmed to control the remainder of the typewriter unit interposers.

It is still a further object of the present invention to provide an improved typewriter input logic system wherein output signals therefrom to the interposer units may be inhibited in certain modes or operations of the writing system.

It is still another object of the present invention to provide an improved typewriter input logic system wherein the typewriter clutch coil is actuated from signals derived directly from the output signals to the interposer units.

The writing system is provided with certain automatic operations or functions which may be coded into the paper tape being passed through the reader unit and include such functions as index, tab, upper shift, lower shift, carriage return, space, back space, print restore, nonprint, skip stop, tape skip, reader on, punch on, punch off, delete code and stop. While these system functions are those which are normally incorporated into a writing system of the type illustrated, it is to be understood that any other functions which the user may desire to incorporate into the system, may be provided. For example, it may be desired to turn an arithmetic unit on or off or control certain functions thereof and any unit of the type which are adapted to be controlled by electrical signals may be controlled through the additional circuit in the function control logic of the system.

The machine function coded signals sensed by the reader unit are fed to a function logic circuit by means of interconnections to the reader input logic circuitry. In the specific embodiment illustrated, a plurality of gate units are provided with inputs from each of the three bit sections described above, which sense the coded information signals being passed through the reader unit. When a machine function signal is sensed, the machine function logic units provide an input signal to the machine logic circuit which generally comprises a plurality of bistable storage devices. However, in certain situations the function signals are fed directly to the operating mechanisms or coils of the particular unit involved directly through logic devices. These latter signals are utilized in the situation where a pulse is required rather than a prolonged

signal. The outputs of the bistable storage devices or the logic units are fed in certain situations, through current amplifying devices, to the operating coils of the particular function involved.

In certain other situations, the bistable storage devices are interconnected to provide a correlation between certain functions of the machine, as for example, in the situation of the nonprint and tape skip modes of the writing system. Thus, when the user desires to put the system into the tape skip mode, the nonprint bistable device is also affected to include the function of nonprint, thus utilizing certain circuit components for dual purposes. In the situation of the nonprint and tape skip modes, the above mentioned bistable devices provide certain inhibit signals to the writing system such as inhibiting the output to the typewriter unit interposers, as described in conjunction with the typewriter input logic section, and also to inhibit the machine function described above in connection with the machine function logic circuit. The system is also provided with a capability of automatically returning to the normal operation of the writing system, and in this situation a print restore or skip stop signal is sensed by the reader unit and fed to the typewriter function logic circuit to reset the bistable devices which were switched by the sensing of the nonprint and tape skip coded signals.

Inasmuch as only one reader may be utilized at any one time to provide input signals to the writing system, it has been found that a single reader on code may be used. This is accomplished by impressing the reader signal into a bistable storage device which is switched with each input pulse being fed to a single input terminal. One such device illustrated as a preferred embodiment, may consist of a diode steering network connected to a flip-flop unit wherein each pulse being fed thereto switches the unit from one state to the other and back again to provide an output signal which sequentially switches from one output terminal to the other. Accordingly, the main reader unit may be connected to one output terminal and the auxiliary reader unit to the other output terminal and the reader units will be switched on in accordance with the pulses received at the input terminal to the flip-flop unit.

The main punch unit is controlled by an information storage device which receives an input signal from the reader input logic circuit to switch the device and thereby switch the main punch unit on. As it is often desired to also provide an auxiliary punch unit simultaneously operating with the main punch unit, a second storage device is provided to control the auxiliary punch unit. However, it has been found that the operation of the punch unit is facilitated, where it is desired to either switch the operating punch from one to the other or turn the operating punch or punches off, by providing a single punch-off signal to reset both bistable storage devices controlling the punch units. Accordingly, if it is desired to switch from one punch unit to the other, a punch-off signal is first read in the reader unit to turn whichever punch unit is operating to the "off" condition and then a punch-on signal is fed to the desired punch unit to turn that unit on to the "on" condition.

In certain situations it may be desired to delete certain codes being read in the reader unit from the remainder of the system and to this end a delete code circuit has been provided to delete the undesired code. One such instance is present where a particular code has been punched into a tape which is adapted to be utilized in a plurality of writing systems. Certain of the writing systems may have one particular function or operation which is coded into the tape while others do not. In the instance where the tape is being used in the system not provided with the particular function or operation, it is desired to delete the code from that particular system and accordingly, the output of the reader output logic circuit is fed to a delete code logic unit.

As will be seen from the following description of the

reader control circuit, it is necessary that a signal is generated each time a particular character is printed or a particular machine function is performed. This signal is necessary to provide a synchronizing signal to the reader control circuit to maintain the synchronism of the reader control circuit and its corresponding functions with the operation of the writing system. One example of the function of the reader control circuit is to advance the reader clutch and thus advance the tape within the reader. If the reader senses a code which does not either print a character or perform a function and is not connected to the delete circuit, the system would stop operation due to the fact that a completion signal is not fed to the reader control circuit.

By way of further explanation, the system has been provided with certain end of function signals such as the end of the index, end of tab, end of carriage return, etc., and where the particular function being performed does not involve the movement of portions of the typewriter unit such as the situation of nonprint, tape skip, reader on, etc., a signal is generated indicating the fact that these signals have been sensed in the reader unit and are to be performed by the writing system. This signal is in turn fed to the reader control circuit to advance the tape and provide the strobing and resetting signal for the logic circuitry and bistable storage devices respectively.

Accordingly, it is still a further object of the present invention to provide an improved writing system function circuitry.

It is a further object of the present invention to provide an improved system function circuit which facilitates the operation of the writing system and improve its reliability.

It is another object of the present invention to provide an improved system function logic circuit wherein completion signals are generated therein to synchronize the operation of certain portions of the writing system.

It is still another object of the present invention to provide a system function circuit which correlates certain functions of the writing system through the interconnection of circuit units controlling those particular functions.

It is still a further object of the present invention to provide a system function circuit wherein certain portions of the system are inhibited in their operation in response to either of two coded function signals.

It is still another object of the present invention to provide a reader on-off control circuit for a main and auxiliary reader unit which utilizes a single reader code signal.

It is still another object of the present invention to provide a main punch and auxiliary punch control circuit wherein a single punch-off code signal will turn either the main, the auxiliary or both the main and auxiliary punches off.

It is still a further object of the present invention to provide an improved system function circuit which generates function completion signals to control the synchronism of certain portions of the writing system in accordance therewith.

At a certain point in the cycle operation of the reader system, it is necessary to strobe all of the reader logic circuits to transmit the information forward to the typewriter logic to operate the imprinting mechanism thereof and also to forward the information to the system function circuit to perform certain functions in the system. The aforementioned strobing operation is a necessity due to the fact that certain portions of the information obtained from the tape being read may be sensed late in the cycle or certain spurious information may be introduced, thus giving a false output signal. The reader logic strobe signal is synchronized with the operation of the reader unit to strobe the information contained in the reader input bistable information storage devices at such time when it is insured that the reader has sensed the

information in a particular code position in the tape. Also, a signal generated to advance the tape reader unit must be synchronized with the operation of the writing system, particularly the typewriter unit, in order to insure the fact that the character has been printed in the case of a character code signal or that the machine function has been performed in the case of a function signal.

In the situation of a character signal, the tape is advanced every 65 milliseconds, 65 milliseconds being the maximum cyclic rate of the reader unit. However, in the case of the system function signals, it is necessary to allow sufficient time for the machine functions to be performed which, in many instances, take a greater time than the normal 65 millisecond cycle time of the reader. For example, it takes approximately 580 milliseconds for the carriage to return from one extreme to the other and it is undesirable that the reader clutch be advanced to advance the tape during this period. Accordingly, certain end of function signals or completion of function signals, are generated by devices sensing the completion of the function, and these signals are fed to the reader control circuit to pulse the circuit and synchronize the operation of the reader control circuit. Thus, a reader clutch signal will not be generated until such time as the functions have been sensed as being completed. As was stated above, certain of these end of function signals are generated in the system function logic circuit such as the reader on, tape skip, nonprint, punch on, etc., functions. In this way, the system is maintained in complete synchronization with the remainder of the system and the tape is inhibited from advancing until such time as the previous code sensed has had sufficient time to allow the circuitry responsive thereto to complete its operation.

To accomplish this purpose, the reader control circuit has been provided with a control loop which is pulsed in accordance with the completion signal described above, whether the signal be of the 65 millisecond duration or longer. The operation of the control loop generates a reader clutch signal in a certain period of the cyclical operation thereof and at some later time generates a strobe signal to strobe the reader logic circuit and thus advance the information stored in the bistable storage devices. The delay between the reader clutch signal and a reader strobe signal is inherently incorporated into the circuit by means of certain delay devices having a fixed period, as for example, a single-shot, or monostable, multivibrator. Thus, the information is strobed the same time in the cycle after each reader clutch signal has been fed to the reader unit. The control loop is a closed loop, thus incorporating a built-in resetting feature for the loop, thereby preparing the circuit for the next cycling pulse.

An initial starting circuit for the control loop is provided wherein a starting signal is fed to the control loop to initially set the conditions therein and initially advance the reader clutch one step. In addition, an initial signal is generated to strobe any information which may be contained in the bistable devices. In certain situations, it may be desired to continuously cycle the control loop and a circuit has been provided to provide a continuous pulsing signal to the control loop, thus performing all the functions incorporated therein without the necessity of generating the completion signals described above. Also, the reader control circuit has logic means incorporated therein which correlates the operation of the punch clutch output signal with the reader strobe signal to preclude the system from going into the nonprint or tape-skip mode prior to the generation of both of these signals. Accordingly, these two signals are correlated by an "and" logic circuit to provide the removal of an inhibit signal to the nonprint and tape-skip function circuits. This inhibit signal is not removed until such time as both the reader clutch signal and the reader strobe signal have been generated.

The reader control circuit is further provided with an initial condition setting circuit which is actuated by the

initial power turn on of the system. Thus, when the power is turned on, a spike is generated and fed through a plurality of circuits to the bistable storage devices of the writing system. In this way the initial conditions of the writing system are set by a single set circuit which is actuated by the initial turn-on to the circuit. Also, this initial power turn-on spike is utilized to reset the writing system in the situation where an error has been sensed by a parity check circuit. Thus, an error is cleared from the writing system by merely turning the main power off and then turning the power back on to generate the initial setting pulse for the bistable storage units.

Accordingly, it is another object of the present invention to provide a means for synchronizing the operation of certain portions of the writing system.

It is still another object of the present invention to provide a control circuit wherein a signal is generated to simultaneously transmit each group of bits of information from one portion of the writing system to another.

It is still a further object of the present invention to provide an improved control circuit wherein a signal is generated to advance the reader clutch in synchronism with the operation of the writing system.

It is still another object of the present invention to provide an improved writing system control circuit which is cyclically operated by a signal corresponding to the advancement of the tape being passed through the reader unit and the advancement of the clutch shaft or by signals generated in response to the completion of certain machine functions or by signals generated in response to the start of certain other system functions.

It is still a further object of the present invention to provide an improved system control circuit having a provision therein for inhibiting the operation of the control circuit in response to a signal generated by the completion of each cycle of the control unit.

It is still another object of the present invention to provide an improved reader control circuit which may be continuously cycled, in the absence of the above mentioned function completion signals, by the generation of a signal in response to certain other machine functions being performed and impressed on the reader control circuit.

It is still another object of the present invention to provide an improved initial condition setting circuit which sets the initial conditions of substantially all of the bistable devices in the writing system.

It is still a further object of the present invention to provide an improved initial condition setting circuit to initially set all of the bistable devices in the writing system upon initial power turn on.

In the situation where the punch unit is to be supplied input signals from the operation of the typewriter unit, it is necessary that coded signals are generated which are representative of either the machine functions being performed or the particular character being printed. Accordingly, the typewriter unit is provided with a plurality of reluctance pickup units, to be hereinafter described, which sense the mechanical movement of certain operating portions of the typewriter. The particular reluctance pickup units illustrated operate through a variation in the reluctance of the air gap thereof wherein an output signal is generated in a coil in accordance with the movement of the typewriter.

Certain of such units are provided to sense the movement of the six bails of the typewriter unit thereby providing a coded output signal having from zero to six bits, in accordance with the movement of from zero to six bails. Also, the machine functions are sensed by reluctance pickup units in proximity to the moving portions of the machine such as the spacing mechanism, the carriage return mechanism, etc. Furthermore, certain other functions of the typewriter are sensed by means of micro-switches, and the like, to produce a similar output signal in accordance with the particular function being per-

formed by the typewriter. Such functions are the tabbing function, the upper and lower shift, and certain punch functions. The outputs of these various signal producing means are fed to bistable information storage devices which change their state in accordance with the sensing or lack of sensing of an input signal.

The output signals from the bail pickup units are similarly fed to a plurality of bistable information storage devices which have their outputs fed, in turn, to a typewriter output logic circuit. The particular signal is coded through the logic circuitry to provide a single output signal which is indicative of the particular combination of bails being actuated. As in the situation with the interposers of the typewriter input logic, the bail sensing logical is grouped into two groups, the first group sensing the movement of the first four bails and the last group sensing the movement of the fifth and sixth bails. Accordingly, the logic devices sensing movement of the first four bails are fed to a plurality of output logic units each having a common input from the logic section sensing the first four bails. However, a second input is provided to the output logic gates which varies in accordance with a reading of bail five, bail six, bails five and six or neither of bails five and six. Thus, for any one group of four output gates, the first gate will indicate the reading in the first four bails and not bails five and six and the second output gate will be indicative of the reading in the first four bails and bail five. Similarly, the third output gate will be indicative of a reading of the first four bails and bail six and the last gate includes bails one to four bails five and six.

This grouping of output gates and bails has been provided in order to economically utilize the electrical components contained in the logic circuit and also to facilitate the interconnection between the output terminals of the typewriter output logic and the input terminals to the punch output logic. The outputs of the various output terminals in the typewriter output logic section may be designated in accordance with the binary equivalent of the coded signal. For example, a reading in channels one, two and three, and not in channels four, five and six will correspond to a binary one in the first three channels and a binary zero in the last three channels. These binary designations may be in turn converted to the decimal equivalents thereof to allow the coded indications of the various signals to be placed on the patch panel. In this way the interconnection between the various logic circuits is greatly facilitated and the user may readily ascertain the particular code configuration of an output signal by merely observing the decimal equivalent thereof on the output patch panel. Similarly, the machine function signals are patched directly to the patch panel and may be decimalized in any manner desired.

Accordingly, it is another object of the present invention to provide an improved typewriter output logic system for use in a writing system of the type described.

Another object of the present invention is to provide a typewriter logic circuit having means incorporated therein to store the input information from the typewriter unit until such time as the information may be strobed forward to the next circuit.

It is still another object of the present invention to provide a typewriter output logic circuit wherein certain machine functions are sensed by means of magnetic pickup units to provide a function signal to the punch unit.

It is still a further object of the present invention to provide a writing system, having certain machine function output signals containing inherent delays incorporated therein, with means for allowing the function to be performed prior to the said output signal.

It still is a further object of the present invention to provide a typewriter output logic circuit wherein a function signal is generated as a result of the operation of a certain portion of the machine, as for example a tabbing

function, and wherein a control signal is fed to the reader control circuit to pulse the circuit. The control signal is provided with an inherent delay therein to allow sufficient time for the function to be performed prior to pulsing the reader control circuit.

5 A still further object of the present invention is to provide a typewriter output logic circuit with a machine function subsystem including a feature such that only one of the functions may be performed at any one time. If two functions are attempted to be performed on the typewriter unit, only the higher order function will be performed. As an example, the delete function will be performed before the stop function in the event both the delete and stop buttons are actuated.

10 15 It is still a further object of the present invention to provide a typewriter output logic circuit wherein the characters imprinted in the typewriter unit are sensed and fed to a logic circuit which develops a single output signal in accordance with the coded input signals from the bistable storage devices.

20 25 It is still another object of the present invention to provide a typewriter output logic circuit wherein a first portion of the logic circuitry is responsive to a portion of the input signals and a second portion of the logic circuit is responsive to the remainder of the input signals.

25 30 It is still a further object of the present invention to provide a typewriter output logic circuit wherein the output logic units are grouped in accordance with the grouping of the reader logic circuits.

30 35 40 The punch output logic circuit is divided into two sections, the first of which accommodates the outputs in accordance with the first six channels of the punch unit and the second portion of the logic circuit adding a bit in the seventh channel, thereby providing a seven channel output. A provision has been made to patch directly into the eighth channel when it is desired to utilize an eight channel output code.

40 45 50 Accordingly, a portion of the output signals from the typewriter output logic section are fed to a first punch output logic section which is adapted to accommodate the punch signals corresponding to the decimal zero to sixty-three code combinations. The higher group of signals, from decimal sixty-four to one hundred twenty-seven, are fed to a second group of norgates forming a second logic section. The second logic section is adapted to have its output fed into the first logic section to duplicate the coded signals provided by the first logic section. Also, output signals are derived in some cases from the input signals to the second logic section or from the output signals from this latter logic section to feed a channel seven logic unit. This latter logic unit is adapted to punch channel seven in the event an input signal is fed to the second logic section. With this configuration, the output signals from the second logic section are fed into the input terminals of the first logic section to provide a coded output therefrom in accordance with the channels one to six output and also provides an output in channel seven.

55 60 65 It is to be understood that the code evolved for decimal zero to sixty-three is in accordance with the binary to decimal equivalent table, as is common in the art, and the codes for decimal sixty-four to one hundred twenty-seven are merely a repetition of the codes for decimal zero to sixty-three plus an information bit in channel seven. In this way the electronic components of the logic circuit are most efficiently utilized and the number of units is kept to a minimum. As was stated above, the logic circuit input terminals may be designated in accordance with the decimal equivalent of the binary output code, which is punched in the punch tape when that particular input terminal is energized. Thus, the user may readily ascertain an output code configuration of a particular input terminal by merely transforming the decimal designation into corresponding binary code.

70 75 The outputs from the punch logic circuit are fed to a

plurality of bistable information storage devices, in the form of flip flop units, which are in turn connected to an output converter unit controlling the operation of the punch coil contained within the punch unit itself. The output gates are controlled in their operation by a plurality of input inhibit signals as for example, a strobe signal, a parity inhibit signal, a punch off inhibit signal, etc. The output circuit is further provided with an auxiliary punch clutch coil which provides an output to the auxiliary punch clutch in the event this punch unit is being utilized.

The outputs of the plurality of bistable flip flop devices are fed to the auxiliary punch unit described above to provide a coded input signal thereto to operate the auxiliary punch in lieu of or in addition to the main punch unit. Also, the outputs of the various flip flop units are fed to a parity check circuit which checks the parity of the output code derived from the flip flop units. If the parity is correct the output is allowed to pass through the logic to the punch coils. However, if the output parity is incorrect, an inhibit signal is generated in the parity check circuit and the punch control circuit to inhibit the outputs to the punch coils prior to their being actuated and thus precluding the punching of erroneous information in the output tape.

As stated above, the output to the punch logic circuit has been provided with a feature whereby channel eight may be actuated in the event the user desires to utilize an eight channel code. To this end, a channel eight logic circuit is provided and input signals are fed thereto from various portions of the writing system, as for example, from the reader input logic or the typewriter output logic. A punch "on-off" switch has been provided wherein the operation of the punch unit may be inhibited by turning the punch switch to the off or open position. With the switch in the open position, a binary one level signal is provided to the inputs of certain of the logic units to inhibit their operations, thus precluding any signals from being passed through the punch logic section. At such time as the switch is closed, the inhibit signal is grounded to remove its effect from the above mentioned logic units and thereby return the punch to its normal operation.

Accordingly, it is one object of the present invention to provide an improved punch output logic circuit for use in a writing system of the type described.

It is another object of the present invention to provide an improved punch output logic circuit which is simple to connect and reliable in use.

It is still a further object of the present invention to provide an improved punch output logic circuit wherein certain of the coded signals are impressed on one portion of the logic circuit and certain other of the coded signals are impressed on a second portion of the logic circuit, the second logic circuit being fed through the first logic circuit to provide a dual use of certain portions of the logic.

It is a further object of the present invention to provide an improved punch output logic circuit which may be expanded from a lesser number of output channels to a greater number of output channels by a simple interconnection of existing components of the system.

It is still a further object of the present invention to provide a punch output logic system for use in a writing system wherein a first group of output signals are generated in accordance with a first code configuration and a second group of output signals are generated in accordance with a second code configuration which includes the first code table.

It is still a further object of the present invention to provide an improved punch output logic circuit which may be readily inhibited during certain modes of operation of the writing system.

It is still a further object of the present invention to provide an improved punch output logic circuit having a parity check feature wherein the output of the punch logic circuit is inhibited in response to the sensing of an

erroneous code prior to punching the erroneous code in the output tape.

It is still a further object of the present invention to provide an improved punch output circuit wherein the auxiliary output is provided with a punch clutch signal having the same inhibit features as the main punch unit.

As was stated above, the outputs of the plurality of punch output flip-flop units are fed to a punch control circuit to provide a pulsing signal and thereby control the operation of the punch control circuit. These output signals are fed through logic circuitry and pulse forming means to provide an output pulse which advances the punch clutch and generates a strobe signal to strobe the information through the logic circuitry. The punch control unit is further provided with a clutch advance pickup unit which generates a signal to reset certain conditions within the punch control circuit. This strobe signal strobes the information contained in the punch output flip-flop units, thus punching and advancing the paper tape contained in the punch unit. The resetting signal is also generated in the punch control circuit which resets the output flip-flop units in the punch output logic circuit to prepare the flip-flop units for the next bits of information from the typewriter output logic circuit.

The punch control circuit is further provided with a signal producing means and keyboard lock means which is responsive to the parity check circuit to provide a system lockup at such time as the parity check circuit indicates that an incorrect parity has been received in the punch output logic circuit. The system lockup circuit generally comprises a logic unit having an input from the parity check circuit and a plurality of inputs from the punch control circuit which operate to coordinate the function of the logic circuit with the operation of the punch control circuit. At such time as the proper conditions are received at the input to this latter logic unit, an output signal is fed to an information storage device, the output of which is connected to a keyboard lockup solenoid which precludes any manual information from being fed into the typewriter unit.

A further signal is generated by the keyboard lockup circuit to inhibit the operation of the reader control circuit, as for example by inhibiting the output signal to the reader clutch, and further provides a signal to the reader control circuit which simulates the operation of the reader stop button. Thus the operation of the reader control circuit is stopped by the signal from the system lockup circuit and the control circuit must be restarted by turning the writing system off and then turning the system back on again. This operation is necessary due to certain features built into the reader control circuit. The resetting function of the punch control circuit is not affected by the parity check circuit inasmuch as it is desired to reset the flip-flops contained in the punch output logic circuit to eliminate the erroneous information being stored therein.

Accordingly, it is another object of the present invention to provide the writing system of the type described with an improved punch control circuit.

It is a further object of the present invention to provide an improved punch control circuit wherein the operation of the punch control circuit is synchronized with the operation of the reader unit and typewriter unit.

It is still a further object of the present invention to provide an improved punch control circuit which is reliably responsive to all combinations of signals being fed to the punch unit including a zero code wherein none of the punch coils have been actuated.

It is still a further object of the present invention to provide an improved punch control circuit wherein the operation of the punch clutch is separate from the operation of the resetting and strobing functions of the circuit.

It is still a further object of the present invention to

provide a punch control circuit which is capable of being inhibited at such time as an erroneous code is sensed by the parity check circuit.

It is still another object of the present invention to provide an improved punch control circuit incorporating system lockup features which are responsive to an erroneous parity being sensed and wherein the reader control and punch control circuits are inhibited by signals generated in the system lockup circuit.

It is still a further object of the present invention to provide an improved punch control circuit having inherent delays built therein to compensate for certain modes of operation of the writing system.

The particular reader unit which is presently preferred, generally comprises a unit which is adapted to be actuated to pass a coded information means therethrough and sense certain coded conditions recorded by, for example, punched holes in the coded information means. While this system will generally be described as utilizing a coded tape, it is to be understood that a punch card or any other type of coded information input storage means may be adapted to provide a changed condition in the circuitry of the reader unit. In one form of the invention, a system for generating coded light beams is utilized to control the reader unit. However, the invention is not so limited. The reader circuit, in one preferred embodiment, includes a plurality of light sensitive devices, such as a plurality of solar cells, which are adapted to respond and generate signals in accordance with the impingement of light thereon. When the light impinges on a particular solar cell, the electrical characteristics of a circuit are affected such that an output pulse is realized at output terminals of the channel corresponding to the particular solar cell energized. Thus, an output pulse is produced which will energize the reader input logic circuitry described above.

A plurality of transistor switching means are connected in responsive relation to the individual solar cells, more particularly the solar cells are connected to the base emitter circuit of the transistors and the transistors are biased in accordance with the electrical energy generated by the solar cell. However, the solar cells do not generate a sufficient voltage to completely bias the transistors to the operational outputting state. This partial biasing has been provided in the reader unit as it is desired to defer the generation of an output signal until such time as a strobing signal may be generated, thus insuring that the output signals are pulsed simultaneously. To this end a strobbing circuit has been provided which provides an additional bias to the base circuit of the transistor which is sufficient to switch the transistor to the outputting state. In the preferred embodiment, the outputting state exists when the transistors are switched to a nonconductive state thereby impressing an output signal of approximately twelve volts, to be hereinafter referred to as a binary one level signal or logical one level signal, at the output terminals of the reader unit.

With the particular circuit parameters chosen for the preferred embodiment illustrated, the transistor is normally in a saturated condition wherein the output current is being shunted to ground through switching transistors. At such time as the solar cells generate a biasing signal, the transistors are converted to the nonsaturated state, however, they maintain their conduction due to the fact that the biasing signal is insufficient to turn the transistors completely off. At a particular period of the reader cycle, a strobing signal is generated and fed to a switching transistor which is connected in biasing relation to the output transistors. The signal generated by this latter switching transistor, or strobing transistor, is removed and at this time the biasing signal generated by the solar cells is of sufficient magnitude to switch the output transistors to the nonconducting state thereby providing an output signal at the output terminals of the reader unit.

Accordingly, it is one object of the present invention

to provide an improved reader unit for use in sensing coded information in an information storage input means.

It is another object of the present invention to provide an improved reader unit for providing output signals in accordance with information coded in an information storage input means, wherein the code is sensed by directing light through holes perforated in the storage input means, the light impinging on a plurality of light sensitive signal generating means.

It is still a further object of the present invention to provide an improved reader unit, for sensing information coded in an information storage input means, the coded information being fed to a plurality of logic type devices which are responsive to both a signal generated in response to the information coded in the information storage means and a signal generated in response to the particular position of the information storage input means.

It is still a further object of the present invention to provide an improved reader unit, for use in generating signals in response to coded information in an information storage input means, wherein a plurality of semiconductor switching devices generate output signals in response to the coincidence of signals generated in accordance with the coded information in the information storage input means and signals generated in accordance with the position of the information storage means within the reader unit.

It is still a further object of the present invention to provide an improved reader unit, for use in generating output signals in response to information coded in an information input storage means, wherein a plurality of semiconductor devices are in a normal conduction state, are rendered to a second conduction state in response to a signal generating means which generates signals in response to the information coded in the information storage input means and are rendered to a third conduction state in response to the addition of a signal generated in response to the position of the tape within the reader unit.

The presently preferred punch unit for use in the writing system illustrated generally comprises a plurality of punch coils which are disposed in controlled relation with a plurality of semiconductor switching devices wherein the conductive state of the semiconductor switching devices energizes the coils to punch a particular channel in the punch unit. The switching devices are representatively illustrated as a plurality of transistors which have their base emitter circuits connected in signal receiving relation to a plurality of input terminals connected to the punch output logic circuit. It is to be understood that PNP transistors may be utilized in lieu of the NPN transistors illustrated. The transistors are normally in the nonconductive state, and, when a signal is impressed on the input terminals, the transistors are rendered to the conductive state to punch the particular channel of the punch unit. Inasmuch as the input signals to the punch unit are simultaneously fed thereto it is not necessary to strobe the signal through the punch unit, but this strobing function is provided by the punch control circuit through the punch logic circuitry. The punch clutch is similarly connected to a switching device which is responsive to an input signal and when the signal is impressed on the input terminal the punch clutch is actuated to advance the output information storage device through the punch unit, as for example, a tape, punch card or the like.

The punch unit further contains a punch clutch reluctance pickup unit which generates an output signal in response to the actuation of the punch clutch to provide a completion signal for the punch control circuit. Also the punch unit has been provided with a selective grounding circuit for certain channels of the punch unit wherein these channels may be fed with a pulsed form of electrical energy or continuously grounded in accordance with the desires of the user. In this way a second code may be impressed on the punch unit in addition to that

derived by means of signals impressed on the input terminals.

Accordingly, it is one object of the present invention to provide an improved punch unit for use in a writing system of the type described.

It is still a further object of the present invention to provide an improved punch unit wherein each of the punch coils are in circuit controlled relation with a semiconductor switching device.

It is still a further object of the present invention to provide an improved punch unit which has the capability of receiving a plurality of codes into a certain of the channels thereof, the codes being in multiplexed relation, one to the other.

It is still a further object of the present invention to provide an improved punch unit for use in a writing system of the type described which has a low heat generating characteristic and is reliable in its operation.

As was stated above certain mechanical operating parts of the typewriter unit, reader unit and punch unit provide output signals to the reader control system and also to the punch control system to indicate a particular sequence of bails being operated, the completion of a machine function being performed, and certain other functions of the system. It has been found that these various signals may be effectively generated by providing a magnetic reluctance pickup unit in proximity to the various operating portions of the writing system, the reluctance pickup unit being in magnetic circuit with the operating portions of the various units.

The pickup unit generally comprises a core member which is in magnetic circuit with the particular portion of the machine, the movement of which is being sensed. An additional magnetic insert is provided which follows the movement of the moving portion of the machine to chop the flux produced by the pickup coil, thus varying the reluctance of the path. The flux in the magnetic circuit is generated by means of a flux producing means, as for example a permanent magnet or an electromagnet, the permanent magnet preferably being formed of grain oriented sintered material. As can be seen from the foregoing description, the reluctance of the magnetic path is varied in accordance with the movement of the portion of the machine. A pickup coil is concentrically supported relative to the core member and produces an output signal in response to the variation of the reluctance of the magnetic path.

While only a few of the reluctance pickup units have been illustrated in detail, as for example, the bail reluctance pickup units, the start and end of the carriage return reluctance pickup unit, the print shaft reluctance pickup unit and the reader cam reluctance unit, it is to be understood that the reluctance units are provided in many other areas of the writing system as will be particularly seen from the detailed description of the writing system. In the situation where the reluctance pickup units are sensing rotary motion of the portions of the machine, as in the case of sensing the angular or rotating movement of a shaft, a cam member has been provided at the end of the shaft with a lobe formed thereon which is adapted to selectively move into proximity with the core of the reluctance pickup unit and thereby change the reluctance of the magnetic path in accordance therewith. In the situation where a start and end of movement is sensed, as in the case of the start and end of the carriage return function, a pair of reluctance pickup units is provided which are spaced one from the other and are in proximity to both ends of travel of the particular portion of the machine being sensed.

Accordingly, it is one object of the present invention to provide an improved magnetic means for sensing the movement of various portions of the unit incorporated in a writing system of the type described.

It is another object of the present invention to provide an improved magnetic pickup means for providing a

coded output signal in accordance with the output of the typewriter unit.

It is still a further object of the present invention to provide a reluctance pickup unit wherein the core thereof is in magnetic circuit with the moving portions of the machine and a pickup coil senses the change in reluctance of the magnetic path in response to movement of the portions of the machine.

It is still a further object of the present invention to provide flux producing means for a magnetic pickup unit which is of a particular configuration and material to allow the reluctance pickup unit to be formed as a compact unit.

The writing system has been provided with certain auxiliary features which allow the user to select certain signals from both the reader input logic section and the typewriter output logic section for deletion from the punch logic circuit to eliminate these signals from the coded storage output means being formed by the punch unit. This select/all circuit is provided with switching means to selectively switch the circuit to respond to a first group of signals, a second group of signals or a combination of the first and second group of signals. Also the writing unit has been provided with a parity check circuit which is adapted to check the parity of the output signals being fed to the punch unit to determine whether the output signals conform to the configuration of code signals chosen for the particular system. The particular parity check circuit which is presently preferred is adapted to distinguish between an odd or an even parity code, that is, where the code being utilized utilizes either an odd number of channels or an even number of channels for each coded signal.

The writing system has also been provided with data feed control circuits which permit the use of data cards in both the reader and the punch units. Accordingly, a stack of coded input cards may be fed through the reader data feed control unit to actuate the reader unit in a manner similar to that done by the coded paper tape. A similar operation is performed in the punch unit wherein a data card is punched in a manner similar to the punching of the paper tape. The data feed control circuits are provided with switching mechanisms to automatically feed the cards through the respective units and also to properly position the cards within the unit at the start of each card cycle. With the card feed features, a printed page may be produced from a punch card and an identical punch card may be produced in the punch unit or a tape may be produced from the punch card being fed through the reader unit. Thus the versatility of the writing system is greatly increased in that data processing capabilities of the system are enhanced by the use of punch cards.

Accordingly, it is one object of the present invention to provide a writing system of the type described with the capability of deleting selected signals from the typewriter input logic circuit and thus from the typewriter unit or from the punch output logic circuit and thus the punch unit, or both.

It is still another object of the present invention to provide an improved writing system of the type described wherein the parity of the coded signals being fed to the punch unit thereof are checked for accuracy and control signals are generated in accordance therewith for use in controlling the operation of the writing system. These control signals may be fed to various portions of the writing system to inhibit the operation thereof in the event that an indirect parity has been sensed.

It is still a further object of the present invention to provide a writing system of the type described with data feed control means which are adapted to expand the writing system to include the processing of other forms of stored data from the punch tape type.

It is still another object of the present invention to provide a writing system having data storage feed means which may be adapted to both the reader and the punch

units and thus allow punched cards to be fed through the writing system both through the reader and punch units.

The writing system of the present invention has further been provided with a format control system which is generally a digital coordination means responsive to certain functional operations of the typewriter unit. These functional operations may include those relating to the indexing of a sheet of paper from line to line and to the spacing of the printing mechanism or carriage mechanism along any given line from character printing position to character printing position along that given line. The general concept of the format control system is evolved from and based on the fact that a sheet of paper which is being fed through the typewriter unit may be divided into individual printing spaces. These printing spaces may be accurately located by a coordinate system defined by an axis parallel to the vertically spaced lines for the "Y" or ordinate and the step-by-step horizontal lines defined by the motion of the character imprinting mechanism for the "X" or abscissa.

Accordingly, any particular type of imprinting space may be located digitally by an "X" and "Y" coordinate as defined by the line-to-line movement of the platen and the step-by-step movement of the character imprinting mechanism. In a writing system provided with a format control system, it is necessary that a plurality of control systems be provided for the typewriter unit, as for example, the main reader control and "X" and "Y" reader units which are adapted to be coordinated with the step-by-step movement of the carriage mechanism and the rotary movement of the platen respectively.

In a preferred embodiment of the format control system of the present invention, a "Y" coordinate or vertical reader unit is mechanically connected to the rotary motion of the platen and closely follows the operation thereof in response to the indexing function of the machine. Similarly a horizontal or "X" reader unit is mechanically connected to closely follow the step-by-step motion of the carriage mechanism. As is readily apparent, with a coded paper tape inserted into both the horizontal and vertical reader units, the signals generated in the auxiliary reader units may be designated by the "X" and "Y" coordinates, respectively. The output signals generated by these reader units may be coordinated, as for example by an "and" type of logic device to provide an output signal which is indicative of the particular character printing space on the sheet of paper. With these signals, a function may be performed at the particular space or an automatic control system connected to the writing unit may take over the operation thereof and cause certain machine functions and character imprinting functions to be performed. Also, related equipment may be controlled by these control signals to permit the transfer of data or information between separate systems and the separate systems' particular portions of the writing system.

The format control system is initially programmed by generating vertical and horizontal tapes in the punch unit which are adapted to be inserted into the vertical and horizontal reader units, respectively. The vertical and horizontal tapes are initially generated by inserting a piece of paper, which is designed to be coordinated, into the platen of the machine and at the starting point of the paper. Each horizontal line or index line of the paper is designated by a particular code punched into the vertical tape, as for example numeric designations of one to nine and then alphabetical designations for the remainder of the index lines of the sheet of paper. Also the horizontal tape is similarly generated in that each horizontally spaced character imprinting space is designated by a particular code signal. The horizontal tape being generated in the punch unit of the writing system is punched in strict accordance with the position of the paper in the typewriter unit.

Thus with each of the vertical lines of character imprinting spaces being designated by a particular code, and

this code being sensed by the vertical reader unit, and also with each horizontal character imprinting space being designated by a second code, and this code being sensed by the reader unit in response to the movement of the carriage mechanism, a coordinate signal is generated for each character imprinting space which has been coded into the system. The output signals from the vertical and horizontal reader units are fed to a format control input logic section. Particularly the signals are fed to a plurality of bistable information storage devices which respond to the signals in each channel of the reader units by changing the set conditions of the bistable devices. The outputs of the bistable devices are fed to a logic circuit, in the form of a plurality of norgates, which code the signals in response to the particular channels actuated. Each of the output terminals of the norgates are connected to a plurality of "nand" type logic circuits wherein one output from each of the vertical and horizontal reader units are fed to an individual "nand" circuit. Thus a coordination of the particular ordinate and abscissa signals is provided through the "nand" circuit.

In the situation where it is desired to perform a machine function at the particular coordinate chosen, the output of the corresponding "nand" gate is fed to a machine function logic circuit. This latter logic circuit is provided with an output terminal connected to the corresponding input terminal of the machine function logic circuit described in conjunction with the typewriter input logic. Accordingly, the particular machine function is actuated by the coordinate signal generated from the vertical and horizontal reader units. In the situation where a character or numeral is desired to be imprinted in the typewriter unit, the output of the "nand" gate is fed to a matrix system, in the preferred embodiment a diode matrix system, to energize a particular vertical leg of the matrix. The horizontal portion of the matrix circuit is selectively energized by a pulsed counting circuit which successively energizes the plurality of horizontal legs of the matrix. The input to the pulse counting circuit is provided from the reader control circuit in response to either a typewriter function pickup signal generated in the reader section or from a signal generated by the print shaft pickup coil.

Thus a sequential operation of outputting signals from the diode matrix is provided in synchronism with the operation of the reader control circuit. The output from the diode matrix is fed to a digital coordinating switch which allows the user to selectively actuate certain character imprinting circuits in the typewriter input logic circuitry. The digital switch may be selectively coordinated to provide a sequence of character imprinting operations wherein the selected information is typed on the sheet of paper inserted into the typewriter unit.

The format control system is provided with a homing feature wherein the complete system, including the reader units for the vertical and horizontal coordinates, may be positioned at a home or start position. With the actuation of the home button, the typewriter unit is provided with a carriage return signal and a continuous indexing signal until such time as a home signal is generated by the vertical reader unit. With the format control system in the home position, the paper is positioned in the platen to an initial starting position thereof and the system is prepared for the desired typing operations. The operation of the format control system is closely synchronized with the operation of the reader control circuit in that the control functions of the reader control circuit are utilized during the operation of the format control system. However, the strobing of the vertical and horizontal reader units are provided by sensing a pulse in channel five of the horizontal reader unit. The reader logic strobe is utilized to strobe the logic circuits of the format control system to transfer information to the "nand" gates.

In the situation where the format control system is being utilized and carriage return and tabbing functions

are being performed it has been found that a provision must be made to inhibit the operation of the reader circuits. This is necessary due to the fact that the platen and carriage mechanism are being operated and the tape is being passed through the reader units due to this movement of the platen and carriage mechanism. Accordingly, an inhibit circuit inhibits the strobing function from channel five of the horizontal reader unit until such time as the carriage return and tabbing functions are completed. Thus spurious information is eliminated from the circuits during the performance of these two functions.

Accordingly, it is one object of the present invention to provide a writing system with a plurality of control systems wherein one of the control systems is associated with the writing system by digital coordination means.

It is another object of the present invention to provide a writing system of the type described with an increased versatility in the programming of printed forms wherein certain character imprinting and machine function operations are common to certain of the forms being passed through the typewriter unit.

It is still another object of the present invention to provide a writing system of the type described with a format control system having the capability of producing and utilizing multiple control signals at any printing space on a sheet of paper.

It is still a further object of the present invention to provide a writing system having a format control system with reader means and digital coordinating means which may be automatically correlated with the relative location of the character and printing mechanism and the position of the platen. The signals generated by the reader means are coordinated by logic circuitry to provide a single output signal which is indicative of a particular printing space on a sheet of paper contained in the typewriter unit.

It is still a further object of the present invention to provide an improved format control system wherein the system has a capability of being homed to a starting position with respect to the typewriter unit.

It is still a further object of the present invention to provide an improved logic system for a format control system of the type described.

It is still a further object of the present invention to provide a format control system with a sequentially pulsed output circuit for providing output signals in sequence to the writing system.

It is still a further object of the present invention to provide a novel strobing circuit for the horizontal and vertical readers of a format control system of the type described.

It is still a further object of the present invention to provide an inhibiting circuit in a format control system which inhibits certain operations thereof during the performance of certain machine functions.

It is still another object of the present invention to provide an improved format control system which is simple and reliable in operation.

Further objects, features, and advantages of this invention will become apparent from a consideration of the following description, the appended claims and the accompanying drawings in which:

THE BASIC WRITING SYSTEM

Referring now to the drawings, and particularly to FIGURES 1, 2 and 3, there are illustrated the basic units of the writing system which comprises a business machine in the form of a manual input and reproducing means 75, as an electric typewriter, an automatic recorder input means 77, such as a reader unit for controlling the operation of the typewriter in accordance with control signals generated from a coded paper tape 79, and signal receiving reproducing means 81, in the form of a punch unit for producing a coded recordation of the functions and character operations of the typewriter 75 or reader 77 in the form of a coded paper tape 83. The complete writing system is mounted on a common casing 85 which both supports the reader unit 77, the typewriter 75 and the punch unit 81 and also provides a housing for the control circuitry interconnecting the three units, as will be hereinafter described.

The reader unit 77 may be utilized to operate the typewriter 75 to produce a printed page and also to reproduce the paper tape 79 in the punch unit, as is conventional in systems of this type. Also, either the typewriter unit 75 or the punch unit 81, or both, may be disassociated from the system to produce either a page print or a coded paper tape or neither, wherein in the latter case, the tape 79 is merely advanced through the reader. The basic writing system is particularly described in detail in copending application Ser. No. 227,767, filed Oct. 2, 1962, the description of which is specifically incorporated herein by reference. Both the reader unit and the punch unit are of the type wherein the output signal is produced by a light sensitive system in the former case and the tape is punched by a plurality of punches, the electrical circuitry of which will be hereinafter explained.

Specifically, the reader unit comprises a means for sensing the presence or absence of a hole in the tape, this sensing function being accomplished by projecting a beam 60 of light through the apertures punched in the tape, the light impinging on a light sensitive device on the opposite side of the tape. Suitable provision is made for advancing the tape through the reader unit and electrical signals are generated by the light sensitive device. These electrical signals are utilized to cause selective energization of certain portions of the typewriter and to provide certain control functions within the typewriter and for actuating means interconnecting the control circuitry and the typewriter operating mechanism. The punch tape system is 65 generally a reproduction system wherein a prepunched tape is fed to the reader section to duplicate the information provided therein in a page print form on the typewriter unit, or provide an identical tape or both. However, in accordance with certain features of the invention, 70 certain signals produced by the reader may be deleted

from either the typewriter or punch units according to a particular programmed sequence of operation. Also, the reader means may be provided with certain control signal functions on the tape itself wherein the electrical signals generated thereby are utilized to perform control functions of the system as a whole, such as turning the punch unit on or off or turning an auxiliary punch, and the like. This type of operation will be readily apparent as the description proceeds.

The typewriter unit 75 is illustrated as being of the type driven by an electric motor (not shown) from a common source of power wherein the typewriter is manually actuated by a typewriter keyboard 90 having a plurality of keys thereon which are suitably identified as to the character which is desired to be imprinted or function to be performed. A plurality of system control keys 92 and 94 are provided on the keyboard to control certain functions of the machine and also to provide on-off switches or certain portions of the typewriter mechanism. A character imprinting mechanism 98, such as for example, a spherical type head is positioned in imprinting relation to an indexing means such as a platen 100 which is adapted to receive a sheet of paper in printing relation to the type head 98. The platen is representatively illustrated as being of the fixed type in the spacing relation and rotatably movable in the indexing relation to the type head. It is to be understood that indexing in the sense being utilized herein is intended to mean the rotation motion of the platen and paper with respect to the type head in its character imprinting position with respect to the paper. The spacing term is intended to be generic to the movement of the paper relative to the character imprinting means in its character imprinting relation thereto and while the platen 100 is illustrated as being of the fixed type, it is to be understood that other types may be used such as the type wherein the platen is linearly movable relative to the main portion of the typewriter unit.

The spacing function is provided by a movable carriage 104 which supports the type sphere 98 and is linearly movable with respect to the platen 100. The spherical head 98 is angularly positionable to provide the proper positioning of the desired character with respect to the paper and the head 98 is also tiltable to a plurality of positions to enable a plurality of rows of type to be utilized on the type head. Thus, the carriage 104 is movable along the rotatable platen in step-by-step fashion from printing space to printing space, and in one motion to the start position on activation of the carriage return mechanism. A pair of control knobs 108 and 110 are provided to manually index the platen 100, the platen 100 also being automatically indexible by a conventional mechanism within the typewriter unit itself. The details of operation for the most part are specifically recited in the aforementioned copending application, and it is unnecessary to an understanding of the invention for those skilled in the art to recite the specific mechanical details of the reader unit 77, the typewriter unit 75 and the punch unit 81.

A second signal generating control system is mounted on the common casing of the typewriter unit and located at the rear and either side thereof and comprises a first signal generating means in the form of an ordinate reader unit 114 and a second signal generating means in the form of an abscissa reader unit 116. The ordinate signal generating unit, specifically a vertical reader 115, is mounted on a bracket 118 in operative relation to the typewriter indexing means, the platen 100, and the abscissa reader unit is mounted on a second bracket 120 in operative relation to the movable carriage 104. The operation of the ordinate reader unit is directly mechanically connected to the rotating motion of the platen 100 and the operation of the abscissa unit is tied directly to the linear movement of the carriage means 104.

In general terms, the ordinate or vertical reader unit 114 and the abscissa or horizontal reader unit 116 form a part of a format controlled writing system which will be

hereinafter described in greater detail. However, for purposes of generally understanding the operation of the total system, a brief description of the mechanical portion of the format controlled writing system, hereinafter referred to as the FCS, will be presented at this time. As was stated above, with a piece of paper engaged in the platen and the platen actuated for its indexing function and the carriage mechanism 104 actuated for its step-by-step function, it is seen that an "X" and "Y" coordinate system may be developed on the piece of paper wherein the platen follows the "Y" coordinate direction and the carriage mechanism follows the "X" coordinate direction. With the generation of a system in this manner, it is seen that the piece of paper may be divided into a line of a plurality of equally spaced, horizontal aligned character printing spaces and a plurality of vertically spaced lines of character printing spaces. Thus, any particular character printing space on the paper may be designated by an "X" and "Y" coordinate.

With the vertical reader means directly and mechanically connected to the rotation of the platen, it is seen that a piece of tape which is placed therein will be advanced both forwardly and backwardly by the forward and backward rotation of the platen. Thus any particular line on a piece of paper may be designated by a position on a piece of tape and a particular function code may be coded into that position on the tape to generate a coded electrical signal in accordance therewith. Similarly, the "X" coordinate system may be generated by following the movement of the carriage mechanism 104. Thus the abscissa reader unit is mechanically connected directly to the back and forth motion of the carriage mechanism and any "X" position on the piece of paper in the machine 75 may be designated by a position on a second piece of tape which has been fed into the abscissa reader unit. Thus, a control signal may be coded onto a piece of paper tape and positioned into the abscissa reader means whereby the relative position of the carriage mechanism will produce an output control signal in the abscissa reader unit by sensing the code punched into the tape at that particular position on the tape. From the foregoing, it is seen that a control function or character printing function may be controlled by the coincidence of a particular "Y" and "X" position on the ordinate and abscissa tape respectively. Suitable control circuitry has been provided to sense the coincidence of a particular position on the respective punch tapes to perform a predetermined function at that particular position of the tapes, as will be hereinafter described. It is to be understood that this secondary control function performed by the ordinate and abscissa reader units are separate from the control function performed by the main reader unit and is operated in conjunction therewith to provide a particular sequence of typewriter, main reader or punch unit functions upon the occurrence of the coincidence of the particular "X" and "Y" tape position.

In order to appreciate the mechanical functions of the ordinate and abscissa tape reader units, the following description of the vertical and horizontal reader units are provided and will be limited at this time to the mechanical operation of the two units. Referring particularly to the ordinate reader unit as illustrated in the upper left portion of FIGURE 1 and the entirety of FIGURE 2, it is seen that the reader unit is generally of the conventional type, differing in the fact that the reader unit is not electrically operated in its advancing of the tape but rather is mechanically operated by a cog wheel-type tape advance 126 mounted within the unit itself. The cog drive is connected to an input shaft 128 which is adapted to drive the cog wheel-type tape driving means 126. A pulley 130 is suitably fixed to the drive shaft 128 by any conventional method and is in driving engagement with a drive chain 132, the chain 132 transmitting a driving force to the shaft 128 through the pulley 130. The driving force of the chain 132 is provided from a second pulley 134

which has been mechanically interconnected with the platen 100 by any suitable gearing means or clutch. A further tensioning pulley 136 is provided on a drive shaft 138 and is utilized to take up any slack and backlash in the chain 132. Thus, as the pulley 134 is driven by the platen 100, the shaft 128 will be driven through the pulleys 130 and 136, respectively. In this manner the mechanical functions of driving the tape through the reader and also providing the other operating functions of the reader, are accomplished.

The reader is provided with a suitable source of light 142 which is focused into the apertures of the reader by means of a focusing mirror 144. For a more detailed explanation of the reader unit, reference is made to the co-pending application, Ser. No. 331,486, filed Dec. 18, 1963, wherein is disclosed a reader unit which may be adapted to be utilized in conjunction with the system discussed above.

Referring now to FIGURES 1 and 3, there are particularly illustrated the details of the abscissa reader unit 116, and specifically a horizontal reader 117, which is connected in driven association with the carriage mechanism 104 to follow the movements thereof. As was stated above, the abscissa reader 117 is mounted on a bracket 120 to locate the reader with respect to the rear portion of the carriage. The bracket 120 may be of any suitable shape to be mounted on the interior cover of the typewriter and is generally formed of stamped metal wherein a plurality of apertures are formed therein to provide screw holes for mounting the various portions of the reader unit. The reader is generally of the type described in conjunction with the ordinate reader, that is, having a cog wheel-type driving means 150 which is adapted to be in driving engagement with a piece of coded paper tape (not shown) which is being fed through the machine.

The rotation of the cog wheel-type driving means 150 is controlled by means of a string 152 which is adapted to be wrapped around a generally flat pulley type member 156 which has been mounted on a shaft 158 common to both the cog type driving means and the pulley 156. The ends of the string 152 are connected to the carriage mechanism 104, one end 160 being attached by means of a fastening assembly 162 to a portion of the carriage mechanism and the other end 166 being attached by a fastening mechanism 168 to a second portion of the carriage mechanism 104. A plurality of pulleys 170, 172, 174 and 176 have been positioned around portions of the exterior of the typewriter unit 75 to provide tension in the string 152 and also to guide the string in its back and forth movement to avoid the possibility of the string becoming bound in any of the operating mechanism of the machine. The pulley 156 is generally axially elongated and is adapted to receive one or a plurality of loops 180 of the string 152 to provide the proper frictional engagement between the string 152 and the pulley 156.

With a piece of coded tape placed in the machine 75 and in driven engagement with the cog wheel-type driving means 150, it is seen that the tape will follow each and every movement of the carriage mechanism 104 as it travels in step-by-step fashion to the various typing spaces along a line defined by the platen, and the tape will further follow the operation of the carriage mechanism in spite of the fact that the carriage mechanism 104 is being returned to a start position each time a line is completed. However, the indexing portion of the carriage return function is not sensed by the horizontal reader unit and it is through the indexing operation that the reader 115 will be advanced.

The horizontal reader unit is provided with a suitable source of light which is concentrated through a light concentrating prism member mounted in the vicinity of the light bulbs to provide a continuous downwardly directed band of light in alignment with a transverse slot in the upper plate of the reader unit itself. It is to be understood that any light directing assembly may be used, as for ex-

ample, a light concentrating mirror or the like. For a system utilizing a light concentrating mirror, reference is made to application Ser. No. 420,579, filed Dec. 23, 1964, by Earl Joseph Schnur. Also, suitable means is provided for guiding the tape through the unit and a light sensitive means is provided within the tape unit to generate an electrical signal in accordance with the particular punched configuration of each of the columns of the coded tape, as is common and well known in the art. The horizontal reader unit is substantially identical to the vertical reader unit and the foregoing application Ser. No. 331,486 may be referred to for a more detailed explanation of the horizontal reader unit.

With the horizontal and vertical reader units interconnected with the operation typewriter unit 75 by means of the platen and its driving assembly and the carriage mechanism and its particular driving assembly, a programmed code signal may be generated at any printing space on the sheet of paper being printed. It is to be understood that the vertical reader unit is to be used repetitively in typing, for example, invoices, form letters, and the like wherein the particular tape punched will be repeatedly fed through the vertical reader unit. Accordingly, the tape may be looped and the ends fastened together wherein the tape is continuously fed through the reader in accordance with the particular movement of the platen. Thus as the platen moves to the next sheet of paper to be typed on from a previous sheet, the tape will be so positioned as to commence a repetition of the signals generated for the vertical position each time the start of a new sheet of paper is received into the typewriter. This type of system is particularly adaptable for a continuous roll of forms such as invoices and the like, wherein certain functions are repeated each time another form is fed through the typewriter unit 75. While such is not the case with the instant embodiment, it is also contemplated that the horizontal reader coded tape may be looped on itself to provide a continuous reading as the carriage mechanism is moved from left to right across the paper in the situation where a repetition of the coded signals is desired for each sheet of paper.

The connecting means between the vertical reader unit 115 and the indexing means 100 of the typewriter 75 comprises, in a preferred embodiment, a nonslip direct chain and sprocket type assembly. The pulleys 130 and 134 are provided with spaced apertures and connecting slots which are adapted to receive the chain balls and links of the chain member 132 to prevent slippage of the chain relative to the pulleys 130, 134. The driving connection between the platen 100 and the pulley 134 may be of the direct gear type such as is in the above mentioned co-pending application, or may be of a releasable clutch type wherein a rubber wheeled clutch is held into driving engagement with the platen by means of a releasable clutch assembly 186. The clutch assembly 186 is adapted to engage a rubber wheel 188 which is nonrotatably connected to a shaft 190 of the plate 100. The operating portion of the clutch assembly 186 comprises a rubber wheel member 192 which is in operative engagement with the wheel 188 and is mounted on a shaft 194, shaft 194 being the shaft on which the pulley 134 is mounted.

The shaft 194 is rotatably supported in a bracket 196 which is mounted on a portion of the typewriter unit 75 and fixedly supports the clutch assembly and pulley 134 in relation to the platen 100. The shaft is selectively movable with respect to the platen 100 by means of a release mechanism 200 which may be of any type to allow the wheel 192 to be moved away from the platen wheel 188. A handle 202 is provided to allow the operator to disengage the wheel 192 from the platen 100 to position the paper within the machine prior to starting thus allowing the coded tape to be fitted into the reader unit 115. In this way the coded tape may be placed into the machine and the platen positioned to relative to the paper prior to the engagement of the wheel 192 with the wheel 188.

31

Thus a starting point may be mechanically established between the tape in the unit 115 and the position of the platen 100 with respect thereto by merely disengaging the clutch assembly with the handle 202. However, it is to be understood that the reader unit 114 may be driven directly by the platen, thus eliminating the clutch unit. In this latter situation, the driving mechanism between the chain and the platen may be incorporated within the platen assembly itself. This may be accomplished by providing a releasable coupling between the platen shaft and the platen roller, thus accomplishing the same alignment function as is accomplished by the clutch mechanism.

Referring now to FIGURES 4 to 7, there are illustrated a plurality of magnetic pickup assemblies which are suitably positioned adjacent certain operating parts of the typewriter mechanism to sense the movement thereof in response to the performance of certain typewriter functions. As the description proceeds it will become apparent that certain machine functions must be sensed to provide a completion of operation signal for the control circuitry of the system and in certain instances it is desirable that a start of the operation signal be provided to signal the start of certain machine functions. For example, it is necessary that a signal be provided for the end of carriage return operation, the upper and lower shift functions, tape advance, print shaft rotation, index, back space, space, the rotation of the punch shaft, to name a few. It has been found to be highly desirable to sense the operation of the mechanism of the typewriter by magnetic means which senses the change in reluctance of its magnetic path, the reluctance being changed by the movement into proximity and away from a pickup coil. Thus, certain operating parts of the typewriter unit itself are moved into and out of the magnetic flux path of a plurality of reluctance units, thereby changing the reluctance of the magnetic path. With the signal thus generated, a plurality of control functions are governed and timed to assure that the operation of the machine is kept in synchronism with the total operation of the system.

Referring particularly to FIGURE 4, there is illustrated a reluctance pickup assembly 210 which is adapted to sense the movement of the several bails, as for example bail 211, of the typewriter. The bail reluctance pickup assembly 210 is utilized to provide a signal which is indicative of the particular bails actuated, the signal being fed to the input section of the typewriter logic circuit, to be hereinafter described. Thus the reluctance pickup assembly 210 provides a coded signal which varies in accordance with the particular character being printed while certain of the other bails reluctance pickup units to be described are of the type which sense particular machine functions, such as those described.

The bail reluctance pickup assembly generally comprises a plurality of pickup coils 212, 214, 216, 218, 220 and 222 which are mounted in spaced relation to but closely adjacent the bails 211 to allow the coils 212 to 222 to sense the movement of the bails. The magnetic flux for the bail reluctance unit 210 is provided by means of a plurality of permanent magnets 224, 226 and 228 which are suitably fastened to a core member 230 by means of nonmagnetic screws 232 which threadably engage the core member 230. The core member 230 is formed of any suitable magnetic material and is formed with a plurality of core brackets 236, which enable the unit to be assembled to the typewriter machine. The magnets 224, 226 and 228 may be of the sintered ferrite type wherein the poles are oriented in a line parallel to the axis of the coils 212 to 222. Thus the magnetic flux path is from the core member 230 through a plurality of core extensions 238, which are concentric with the coils 212 to 222, through the bail units and back to the other side of the magnets 224, 226 and 228.

The bails are provided with a plurality of magnetic insert members 240 which are so positioned as to be utilized to close the gap between the bail and the end of

32

the cores 238 so that the operation of the bails will not be interfered with by any portion of the bail pickup unit. Thus as the bails 211 are activated by the operation of the typewriter mechanism, the insert 240 is moved into proximity of the core 238, thus changing the reluctance of the magnetic path created by the magnets 224, 226 and 228. With the change of reluctance, the flux in the core 230 will vary accordingly and a signal will be generated in the coils 212 to 222. The signal generated in the coils 212 to 222 is utilized to provide an input signal for the typewriter logic section, as will be hereinafter, more fully, described.

Referring now to FIGURE 5, there is illustrated a magnetic reluctance pickup assembly 250 which is adapted to sense the start and end of the carriage return movement. The reluctance pickup assembly 250 generally comprises a pair of individual reluctance pickup units 252, 254, which are responsive to the limits of the motion of a carriage return latch 256, one position of which is shown in solid line and the other position shown in phantom. The lower unit 254 is responsive to the start of the carriage return cycle and the upper unit 252 is responsive to the end of the carriage return cycle. The units 252 and 254 are of the same general construction as those described above, that is, unit 252 comprises a core bracket member 258 having an extension 260 thereon which forms the core member for a pickup coil unit 262. The end of the core member is provided with a pole face which is positioned in close proximity to the upwardmost movement of the latch 256 to sense its movement with respect to the pole 260.

The main body of the core member 258 is provided with a plurality of apertures with which the unit 252 is mounted on the frame or some other member of the typewriter unit 75. As in the above situation, a magnet 264 has been mounted on the core member 258 having one pole oriented outwardly of the member 258 and the other pole mounted closely adjacent thereto. Thus the flux from the magnet will go through the core member 258, including the core 260 concentrically within the coil 262, through the latch member 256 and back through the air to the other face of the magnet 264. The magnet has been mounted on the core bracket 258 by means of a pair of nonmagnetic brass screws 266.

The carriage return start function is sensed by the unit 254 and the latch has been illustrated in phantom to indicate the lowermost position of the latch at the start of the carriage return cycle. As in the above case, the unit generally comprises a core bracket 270 having a magnet 272 mounted thereon which is adapted to supply flux through a coil 274. The coil will generate the output pulse when the carriage return latch is in proximity to a face of the core 276. The core bracket 270 is suitably mounted in proximity to the limit of movement of the latch 256 on some portion of the typewriter machine by any suitable fastening means. FIGURE 6 particularly illustrates a print shaft reluctance pickup unit 279 which is responsive to the rotation of a print shaft 280 mounted within the typewriter. The pickup assembly 279 also comprises a core bracket 282 having a coil 284 mounted thereon in magnetic relation to the flux produced by a magnet 286. In the situation where the rotary motion of the shaft 280 is being sensed, a cam member 290 is mounted on the end of the print shaft and has a lobe 292 formed thereon which is positioned closely adjacent the end of the core bracket 282. Thus as the lobe 292 is rotated into face proximity with the end of the core bracket 282, a pulse will be produced in the coil 284.

FIGURE 7 illustrates a pair of reader cam reluctance units 293, 293' wherein units substantially identical to that provided in conjunction with FIGURE 6, are provided to sense the rotary motion of a pair of cam members 294 and 296, respectively. As in the above situation, the cam members are provided with a pair of lobes 298 and 300 which are adapted to pass in close proxim-

ity to core units 302, 302' having pickup coils 304, 304' mounted thereon. The magnetic flux is provided by means of magnets 306, 206' which are suitably mounted on core brackets 308, 308' by means of nonmagnetic fasteners. The reluctance pickup units are adapted to sense the rotary motion of a reader cam shaft 308 through the pair of cam members 294, 296 thus supplying a pair of signals, one of which is utilized to strobe the reader itself and pass the signals derived from a plurality of light sensitive devices contained therein and the other is utilized to indicate the start of the tape advance through the reader.

THE PUNCH UNIT AND READER UNIT CIRCUITY

As was stated above, the reader unit 77 generally comprises a source of light which is adapted to pass through the code holes punched in the tape and impinge on a plurality of light sensitive devices, such as for example, a plurality of solar cells. When the light impinges on a particular solar cell, the electrical characteristics of a circuit are effected such that an output pulse is realized at the output terminals of the channel corresponding to the particular solar cell energized, thereby producing a pulse which will energize an input logic circuit connected thereto. However, in units of this type, it is necessary that the tape be completely stopped during the reading process and also that all channels be read simultaneously at such time after it is a certainty that all the channels may be properly read. This is required in order that no spurious information be fed from the tape into the reader unit itself. Accordingly, the reader unit of the present invention has been provided with a strobing feature which tends to strobe the output circuits of each of the channels simultaneously to insure that each channel is read at the same time.

Referring to FIGURE 8, it is seen that a plurality of eight transistors 320, 322, 324, 326, 328, 330, 332 and 334 are utilized as amplifiers to control the outputs to a plurality of output conductors 336, 338, 340, 342, 346, 348 and 350 which correspond to eight channels of an eight-channel reader unit. This reader unit is of the type which is preferably utilized in the position shown for reader unit 77. The plurality of transistors, 320 to 334, are provided with a suitable source of positive voltage supply, such as 15 volts, by means of a conductor 352 connected to a plurality of collector resistors 354 connected to the collectors of each of the transistors by means of conductors 356. The emitters of the transistors are connected to a conductor 358 which is connected by a second conductor 360 to ground potential. The transistors 320 to 334 are normally heavily saturated by means of a plurality of bias resistors 364 and 384 connected to the base of the transistor, thereby applying substantially plus 15 volts thereto.

Thus the bias current flows from conductors 352, 366, through resistors 364 and resistors 372, through resistors 384, through the base-emitter circuit of transistors 320 to 334 and thence from conductors 358 and 360 to ground. The collector-emitter circuit, with the transistor heavily saturated, is from conductor 352, through conductor 366, through resistors 354 to conductors 356. The current then passes through the collector-emitter circuit of the transistors 320 to 334 to ground by means of conductors 358 and 360. With the transistors heavily saturated, the output terminals are at substantially ground or at plus. 3 of a volt, the normal drop across the collector-emitter circuit of a transistor of this type. However, when the transistors are nonconducting, it is seen that the plus 15 volts is applied to the output terminals through conductors 336 to 350 to produce an output pulse which corresponds to a reading in that particular channel.

A normally nonconducting transistor 370 is connected across the power supply by means of the conductor 352,

a resistor 372 and a conductor 374. However, with the transistor nonconducting, the connection across the power supply is through resistor 372, resistors 384 and the base-emitter circuit of transistors 320 to 334 and thence from conductor 358 and 360 to ground. However, when the transistor 370 commences conduction, the voltage across the power supply is dropped across the resistor 372 and the collector-emitter circuit of transistor 370 which removes the bias current from the transistors 320 through 334. The voltage on resistor 372 is impressed on the collectors of the various transistors by means of the conductors 366, 356, and it is seen that the conduction of transistor 370 enables transistors 320 through 334.

The transistor 370 is normally nonconducting until such time as a pulse is received through the base emitter circuit from a conductor 378 connected to a reader strobe reluctance pickup unit 380, such as that described above, which is connected to the reader shaft 308, described in conjunction with the description of FIGURE 7. As was stated in conjunction with FIGURE 7, one of the cams, such as cam 296, provides the strobe signal for the reader unit and it is coil 304 that provides the pulse to commence conduction of transistor 370. The duration of conduction of the transistor 370 is of the order of 4 milliseconds and occurs early in the 65 millisecond cycle of the reader unit. Accordingly, with the transistor 370 conducting, the current at the base electrodes of transistors 320 to 334 is dropped due to a certain portion of the base emitter current being shunted by a plurality of resistors 384 which are connected to the base by means of a plurality of conductors 386 and to the collector of transistor 370 by means of a conductor 388. The conduction of transistor 370 and the shunting of a part of the base emitter current enables the transistors 320 to 334 but they remain in saturation by the current supplied by resistors 364. Therefore, the output terminals will still remain at a zero level as in the situation wherein the transistor 370 was not conducting.

A plurality of solar cells 390, 392, 394, 396, 398, 400, 402 and 404 are connected to the base electrodes of transistors 320 to 334 by means of a plurality of conductors 406 and the cells 390 to 404 generate a reverse biasing voltage of approximately negative .3 volt when there is light impinging on the solar cells. The solar cells may be considered a constant current device and do not generate a sufficient voltage to turn transistors 320 to 334 off while transistor 370 is still in the nonconducting state. Thus, even with all of the solar cells or any one of the solar cells energized by light impinging thereon, there will still be no output at any one of the 8-channel output terminals. However, with the coincidence of light impinging on any one of the solar cells and transistor 370 in the conducting state, the corresponding transistor of the group of transistors 320 through 334, will then be turned off and the signal from conductors 356 will be fed to the output terminals 336 to 350 of its corresponding transistor. Thus, the fact that light impinges on one of the solar cells 390 to 404 is insufficient to turn any one of the transistors 320 to 334 off and the single condition of transistor 370 conducting is insufficient to turn any one of the transistors 320 to 334 off. It is the coincidence of these two events which provides an output signal at any one of the output terminals of the eight channels. It is to be noted that while the tape is being advanced through the reader and the light is impinging on the solar cells at any given length of time, it is not until the tape is completely stopped and all of the solar cells which are to be energized are energized, that the transistors 370 is finally turned on to strobe the output of the reader unit into the reader logic section, as will be hereinafter explained. Thus, the operation of the reader circuitry may be considered to be a "nand" gate.

In operation, and assuming channel 6 is energized which would correspond to the energization of solar cell

400, the following sequence of events will occur. At such time as the tape is being advanced through the reader and prior to stopping in the read out position, the transistor 330 in addition to all the other transistors of the group of transistors 320 through 334, will be conducting and a zero output will be present at the output terminal to channel 6. The collector voltage transistor 330 is supplied through the conductors 352, 366, the resistor 354, and the conductor 356. The base-emitter current is supplied through the conductors 352, 366 and the resistors 364, 372 and 384. Both the collector-emitter and base-emitter currents are returned to ground by the conductors 358 and 360. When the tape stops, the solar cell 400 will be energized, but this energization will be insufficient to turn transistor 330 off.

At such time as the reader shaft cam 296 passes the pole 302, an output pulse will be generated in coil 304 which will be fed to the base of transistor 370 by means of the conductor 378. The transistor 370 will then be turned on and the current from the power supply will be fed from conductor 352 through resistor 372, the collector-emitter circuit of transistor 370, conductor 374 and conductor 360. The conduction of transistor 370 applies a voltage across resistor 372 which will be approximately .3 volt less than the plus 15-volt power supply being fed thereto, and this will reduce the current supplied to the base of transistor 330 by resistors 372 and 384. Also, the base emitter current of transistor 330 will be supplied by resistor 364. With the condition of transistor 370 and the energization of solar cell 400, the base voltage of transistor 330 will be dropped to substantially zero or slightly negative, thereby turning transistor 330 off and supplying the voltage from resistor 354 to conductor 356 and output conductor 346. Thus a pulse will be fed to the channel 6 output terminal.

The reader has a clutch unit, as is common in the art, which is magnetically operated by a reader clutch coil 410 connected in series circuit with an NPN transistor driver 412, both of which are connected to a plus 25-volt power supply by means of a conductor 414 and to ground by means of a second conductor 416. A diode 418 has been provided in shunt relation to the reader clutch coil to take up the inductive kick which is normally present in inductive circuits of this type when the transistor 412 is switched to the nonconducting state. An input signal to the transistor 412 is provided by means of a conductor 420 and a current limiting resistor 422, the signal being supplied from a pulsing circuit as will be herein explained. A resistor 424 is connected to the base circuit and to a negative 5-volt power supply to insure that the transistor 412 is totally nonconducting and provide temperature stabilization therefor to preclude thermal runaway.

When the pulse is received on conductor 420, the transistor 412 will be turned on and current will flow through the reader clutch coil 410 and actuate an armature which advances the reader clutch. At such time as the signal is terminated from the clutch, the reader shaft will continue to rotate until the clutch is mechanically reset by the continued rotation of the shaft. Also a tape advance pickup unit 426 has been provided in the form of a reluctance pickup unit, as described above, which senses the start of the advancing of tape through the machine. This tape advance signal is fed to an NPN transistor 428 which has been connected to a suitable source of plus 15-volt power supply by means of a conductor 430. The collector is connected to a source of plus 15-volt power supply by means of a conductor 430 and a resistor 432. The transistor 428 is normally nonconducting but when it is conducting, current passes from the plus 15-volt power supply through the resistor 432 and the collector-emitter circuit of transistor 428. At such time as a signal is received from the pickup coil 426, the transistor is turned on the signal is shunted through the collector-emitter circuit thereof to provide a zero output conductor 434. This latter output signal is provided to control certain portions of the reader

control circuit, as will be more fully explained later in the description.

Referring now to FIGURE 9, there is illustrated a circuit diagram of the electrical circuit 440 which has been incorporated into the punch unit. The punch unit is representatively illustrated as of being the eight-channel type, but it is to be understood that any number of channels may be utilized, four to eight channels being common in the art. Each of the separate punches has a punch coil 442 to 456 in operative association therewith and a plurality of representatively illustrated NPN transistors in series controlling circuit with the coils 442 to 456. The transistors 458 to 472 are normally nonconducting thereby producing a zero current flow through the punch coils 442 to 456.

The collector emitter circuits of each of the transistors 458 to 472 are connected in series circuit with the punch coils 442 to 456, and the conduction of the transistors 458 to 472 is controlled by means of a signal fed to the base-emitter circuit thereof. A source of positive potential is connected to a conductor 474 and this 25-volt potential is electrically fed to a conductor 476 common to all of the punch coils by means of a selector switch 478, which may be of the manually actuated type, as is common in the art. To achieve the selective operation, the switch 478 comprises a movable armature portion 480 selectively movable between positions in contact with an "off" terminal 482 and an "on" terminal 484. When the switch is moved in contact with terminal 484, the 25-volt potential is fed to each of the eight coils.

Each of the emitters of the transistors 458 to 472 are connected to a common conductor 486 which is in turn connected to ground through another conductor 488. The circuit from the positive potential with the switch 478 in the "on" position, thus turning the punch "on" is through conductor 474, terminal 484, conductor 476 to each of the respective coils and collector emitter circuits 442 to 456 and 458 to 472, respectively, through conductor 486 and conductor 488 to ground. The base circuits are fed a pulse through a set of input terminals 490 to 504 and through a set of current limit resistors 506.

Thus, when a positive pulse is received at input terminals 490 to 504, each of the transistors 458 to 472 will be rendered conductive in accordance with the particular input terminals 490 to 504 which have been energized. As will be hereinafter explained, the input pulses to each of the terminals 490 to 504 are fed simultaneously through a strobing circuit in the output circuits connected thereto and the particular channels which are to be energized will be pulsed simultaneously due to this strobing of the output network. Accordingly, any spurious signals which are fed to the output network of the punch unit will not be fed to the punch unit itself, that is, into circuitry 440, as will be hereinafter explained in conjunction with the punch logic circuitry. Each of the coils has been provided with a diode 510 connected in parallel relation thereto to absorb the inductive kick which is realized upon the deenergization of the punch coils 442 to 456.

In certain situations, it is desired to superimpose a second code on the code being fed to the input terminals of the punch circuit 440. To achieve this function, a pair of grounding conductors 512 and 514 have been connected through a pair of diodes 516 and 518 to the terminals 520 and 522 which would be normally grounded when it is desired to actuate channels 3 and 4. It is to be noted that channels 3 and 4 correspond to inputs 494 and 496, respectively. The upper portions of the conductors 512 and 514 are connected to a conductor 524 which may be selectively grounded through a button (not shown) mounted on the typewriter machine itself. Thus when it is desired to continuously punch channels 3 and 4 or to selectively punch channels 3 and 4, a continuous ground or selective ground is placed in conductor 524, thereby punching channels 3 and 4 at the desired times.

A punch clutch coil 528 has been provided in series

circuit with the collector-emitter electrodes of a transistor 530 in a manner similar to the connection of the transistors associated with channels 1 through 8. The collector of transistor 530 is connected to the low voltage side of the punch clutch coil 528 and the emitter of transistor 530 is connected to conductor 486, which is at ground potential. The clutch activation pulse is supplied from an input terminal 532 and resistor 534 through a conductor 536, the series combination being connected to the base circuit of the transistor 530. Thus, when a pulse is received at input terminal 532 the transistor 530 is turned on to pulse the punch clutch. The main supply voltage for the punch clutch coil is supplied by means of the conductor 476. An inductive kick dissipating diode 540 is connected in parallel circuit to the clutch coil as was described in conjunction with the coils of channels 1 to 8. Also, a grounding conductor 542 is connected to the low voltage side of the punch clutch coil 528 and the opposite end of this conductor 542 is connected to a tape feed switch mounted on the typewriter unit 75 or the punch unit 79. This switch may be selectively grounded, thereby grounding conductor 542, to advance tape through the punch unit itself for purposes of providing a lead portion on the punch tape or a tail portion, or merely to skip tape through the punch unit.

As will be seen from a description of the punch unit control circuit, a pulse indicating the completion of the punching of a particular column of bits of information is required to reset certain portions of the control circuit and other logic circuits in order to enable the system to receive the next column of bits of information. The end of the punch cycle is sensed by means of a reluctance pickup unit 544, which is of the type described in conjunction with FIGURES 4 to 7, and the signal generated thereby is fed through a conductor 546 and a diode 548 to the base circuit of a NPN transistor 550. The collector of the transistor 550 is connected to a positive source of 15 volt potential by means of a conductor 552 and resistor 554 and the emitter is connected to ground through a conductor 556. The base of the transistor 550 is connected to a negative source of potential such as a -5 volts by means of a conductor 558 and resistor 560 to assure that the transistor 550 is nonconducting and provide temperature stability. The output from transistor 550 is fed through a conductor 562 to an output terminal 564 for a purpose to be hereinafter explained.

As was stated above, the transistor 550 is normally nonconducting and accordingly, the output potential at terminal 564 will be at approximately +15 volts. When a pulse is received at the base electrode of transistor 550 from reluctance pickup unit 544, the transistor 550 will be turned on and the output terminal 564 will be dropped to approximately ground potential. It is to be understood that the potential will be approximately zero but may be as much as the drop across the collector emitter electrodes of transistor 550, in this case approximately .3 of a volt. The output signal at terminal 564 is to be fed to the punch control circuit, as will be hereinafter explained, and provides an end of function signal which is utilized to reset certain portions of the punch circuit and is further utilized for control purposes to synchronize the operation of the punch unit with the rest of the system. A plurality of resistors 568 are connected to the base circuits of the channels 1 through 8 transistors and the punch clutch transistor to insure that these transistors are cut off during the nonpunching portion of the cycle. This purpose is identical to the purpose of resistor 560, that is, to place the base electrodes of the various transistors 458 to 472, 530 and 550 at a negative potential, such as a negative 5 volts.

A GENERAL DESCRIPTION OF A BLOCK DIAGRAM OF THE COMPLETE SYSTEM

Referring particularly to FIGURE 10, the writing system generally comprises a reader unit 572 which sup-

plies coded output signals to a reader input logic section 574 by means of a reader program board which takes the form of a patch panel 576. The reader input logic section 574 translates the eight channel coded signals to sixty-four separate signals which represent sixty-four combinations of the individual eight channels. The output of the reader input logic section 574 is patched through the program board 576 to the typewriter input logic section 578 which translates the usable portion of the sixty-four output signals to a code related to the particular interposer sequence of the typewriter machine being utilized. Also, the typewriter function signals read by the reader section are fed to a typewriter function logic section 580 through the reader program board 576, the outputs of both the typewriter input logic section 578 and the typewriter function logic section 580 being fed to a typewriter unit 582. The typewriter unit also has a manual input by means of an operator as symbolized by arrow 584. The control of the reader including its reader input logic section 574 and the typewriter input logic section 578 is achieved by means of a reader control logic section 586 to synchronize the operation of the reader with the typewriter unit. Thus a page of typewritten print is produced from signals read from the reader unit 572 including the functional operation of the typewriter 582 from further signals read from the reader unit 572.

The characters being printed by the typewriter unit 582, including its functional operations, may be sensed and fed to a punch unit 588 through a punch program board or patch panel 590 and the punch output logic 600. Also, the typewriter unit 582 may be completely bypassed by feeding the signals read from the reader unit 572 through the reader program board 576 to the punch program board 590 and thence directly to the punch unit 588. The character printing operations of the typewriter unit 582 are sensed by a typewriter output logic section 596 and a punch operation logic section 598, which signals are fed to a punch output logic section 600 through the punch program board 590. These signals are then fed to the punch program board 590 and thence to the punch unit 588. The operation of the logic sections 596, 598 and 600 are controlled by a punch control circuit 602 which controls the operation of the punch unit 588. The accuracy of the signals produced in the punch output logic section 600 are checked by a parity check logic section 606 which checks the parity, either odd or even, of the output bits being received from the punch output logic section and, in the event an incorrect group of bits is received, the punch control circuit 602 is inhibited in its operation.

To describe the block diagram of the system more specifically, the output signals from the reader 572 are fed by means of a plurality of conductors 610, to the reader program board 576 and thence are fed to the input side of the reader input logic section 574, or more specifically, to a set of 8 input flip-flop units 612 by means of a second plurality of conductors 614. The eight outputs from the flip-flop units 612 are fed to a reader output logic circuit 616 by means of a plurality of conductors 618 wherein the eight inputs are first transformed to 20 outputs, which are in turn transformed into 64 outputs by means of logic circuits. The 64 outputs from circuit 616 are fed by means of a plurality of conductors 620 to the reader program board 576 and it is to be understood that the 64 outputs also include not only the character portion of the typewriter operation but also the typewriter function signals. In this regard, it is to be noted that the unused portion of the sixty-four signals, that is those signals not utilized in either the function or character codes, are deleted from the circuit through a delete logic unit. This deletion is performed to generate a cycling signal for the reader control circuit to maintain the operation of this circuit.

The output from the program board 576 is fed, in various combinations to form 132 input signals, to a

plurality of reader input logic, output gates 621 by means of a plurality of conductors 623. The outputs of gates 621 are fed to the input logic circuit 622 of the typewriter input logic section 578 by means of a plurality of conductors 625, which outputs correspond to the character signals. The logic reduces the forty-four signals down to six outputs and a seventh output which corresponds to the clutch of the typewriter unit. The seven output signals are fed to a set of typewriter interposer solenoids 624 by means of a set of conductors 626 to operate the solenoids and manipulate the typewriter. The typewriter function signals, which are approximately sixteen in number, are fed to a typewriter function logic circuit 628 by means of a set of conductors 630, and the signals corresponding to the residue of the 64 outputs are fed into a delete section provided in the typewriter function section 628. The outputs of the typewriter solenoids 624 and the typewriter function circuit 628 are fed directly to the mechanical operation of the typewriter unit 582.

The control of the operation of the circuits just described are maintained by a reader control circuit 634 which is contained with the reader control logic section 586. The reader control circuit 634 provides an output signal by means of one of the conductors of the plurality of conductors 636 to advance the reader clutch, as one example. Also, an input signal is fed from the reader unit by means of the tape advance pickup through one of a plurality of conductors 636 to the reader control circuit, wherein this input signal and the print shaft signal from the typewriter are combined to advance the reader clutch. The basic function of the reader control circuit 634 is to provide a strobe signal to the reader input logic section 574 and also to reset the flip flop units, at the end of the stroke signal, also contained in the reader input logic sections 574. To this end the reader control circuit 634 contains a continuously operating control loop which is pulsed in synchronism with the operation of the reader or in accordance with the completion of certain typewriter functions which are being performed in the typewriter unit itself.

These typewriter functions are sensed by magnetic pickups and the like, and are fed to the reader control circuit to continuously pulse the circuit each time a machine function is performed. Also, the reader control circuit 634 contains a general grounding circuit which initially sets all of the flip-flop units both in the reader section and certain portions of the punch system when the power to the system is initially turned on. In this way the system is readied to receive information from the reader unit. The reader control circuit 634 also receives signals from the punch control logic section 602 by means of conductors 690, as will be hereinafter explained, and these signals are utilized during the period when the punch unit 588 is being used and the typewriter unit 582 is turned off. Thus, the passing of tape through the reader may be continuously performed even though the typewriter unit is not being used, the control signals to control the system being fed from the punch unit through the punch control circuit.

The outputs of the typewriter unit 582 as sensed by the reluctance pickup units to including the character printing operations and the function operations, are fed to a plurality of flip flop units 650 and 652, respectively, by means of a plurality of conductors 654 and 656, respectively. The outputs of the flip-flop units 650 are fed by means of a plurality of conductors 658 to a typewriter output logic circuit 660 which translates the six ball pickup inputs into forty-four output signals. These output signals are fed to the punch program board 590 by means of a plurality of conductors 662. The punch function output signals are fed from the punch function logic section 652 to the punch program boards 590 by means of a plurality of conductors 664, the combined outputs from conductors 662 and 664 being fed to a plurality of decimal designated hubs contained in the punch program board 590. The decimal out-

put hubs in the punch program board 590 are fed to the punch output logic circuit wherein the inputs to the punch output logic section 600 are transformed into eight output signals which are fed to the punch unit itself by means of a plurality of conductors 668 and 670.

The operation of the punch output logic circuit 600 is advanced by means of a plurality of conductors 674 which supplies a plurality of control signals for the punch control circuit 602. The primary function of the punch control circuit 602 is to provide a stroke signal for the typewriter output logic section 596 and a second stroke signal for the punch output logic section 600 through a plurality of conductors 673, 674 thereby synchronizing the operation of both the typewriter output logic and the punch output logic to provide a sequence of passage of information from one to the other. Direct control of the punch unit 588 from the punch control circuit 602 is achieved by means of a conductor 676 and conductor 670. With this signal, the punch unit is maintained in operation through the pulsing of the punch clutch, and a further signal is fed from a conductor contained in the group of conductors 670 and 676 to signal the punch control unit as the punch clutch has completed its operation.

The output from the punch output logic section 600 is also fed to a parity check circuit 606 by means of a plurality of conductors 680 and the parity of the output signals is checked for accuracy. If an inaccurate signal is sensed, the parity check circuit will provide a signal through a conductor 682 to inhibit the output of the punch output logic section and also a further signal is fed to the punch control unit by means of conductors 684 to inhibit the operation of the punch control unit 602. Also, the signal impressed on conductor 684 is fed to a keyboard lock solenoid through proper circuitry contained in the punch control circuit 602 whereby the complete keyboard of the typewriter unit is locked. With the board locked in this fashion, the manual input to the typewriter is precluded until such time as the system is turned off and turned on again to clear all of the flip flop units.

As stated above, the output from the reader section may be fed directly from the reader program board 576 to the punch program board 590 which are fed to the 8 output flip flops in the punch output logic 600, thereby bypassing the typewriter unit. Accordingly, a set of control signals is fed to the punch control circuit 602 by means of a plurality of conductors 688 to control the operation of the punch unit in accordance with the operation of the reader unit. Since the punch unit has a faster cycle time than the reader unit, no synchronizing is necessary.

Certain operations of the system are provided automatically to render the system a format controlled writing system. In this situation, a particular position on the paper in the typewriter unit being printed are sensed by means of a vertical and horizontal reader unit, as described above, and these signals are fed to a format control system 700 by means of a plurality of conductors 702 connected to the vertical and horizontal reader units. These signals are fed through the reader program board 576 to the format control system 700 by means of a plurality of conductors 704. The outputs of the format control system 700 are fed to the typewriter input logic section 578 by means of a plurality of conductors 706 to provide the character printing and the machine function signals are fed by means of a plurality of conductors 708 to the typewriter function circuitry 628. A punch off signal is fed to the punch control circuit 602 by means of a conductor 710 which turns the punch unit off at such time as certain signals are to be fed to the typewriter unit but not to be punched in the paper tape being processed through the punch unit 588. Similarly, certain control functions are performed in the reader control circuit by feeding certain output signals from the format control system 700 to the reader control circuit 634 by means of a plurality of conductors 712. Thus, an automatic control of the typewriter unit and punch unit is provided at such

time as a certain coincidence of signals is received from the vertical and horizontal reader units, as described above and to be more fully described hereinafter.

In the system just described, a complete universality of codes is provided wherein any input unit having a particular code may be made compatible with any output unit having an identical code or a completely different code. Also, a unique system of controls are provided in the reader control circuit 634 and the punch control circuit 602 to fully synchronize the system and provide certain control functions which are necessary for the proper operation of the system. Also, the system provides for the simultaneous passing of information from one stage of the logic circuit to the next information receiving stage to minimize the possibility of extraneous information from entering the system. Further, the most advantageous utilization of the circuit components has been provided to minimize the number of electrical components in the system while still maintaining accuracy in its transmission of information from one unit to the next.

GENERAL DESCRIPTION OF THE COMMON CIRCUIT MODULES

The following description of the common circuit modules provided to facilitate the full understanding of the operation of the system as the description proceeds and to provide brevity thereof. For purposes of simplicity, the voltage levels at various points or on conductors of any circuit will be indicated by the on-off binary designation, that is, where the voltage at any point is approximately zero, in many instances .3 volt, the voltage level will be indicated as being a binary zero (0). Also, if the voltage at any point is approximately positive 12 to 15 volts, the voltage level will be indicated as being a binary one (1). Further, in general all collectors of transistors are supplied by a plus 15-volt supply voltage and all emitters are at ground potential unless otherwise indicated. In each of the module figures, the schematic diagram of the circuit has been shown and its corresponding symbol has been illustrated in the same figure.

Referring now to FIGURE 11, there is illustrated a preferred enabling means in the form of a norgate circuit 720 which generally comprises an NPN transistor 722 having a collector electrode 724 connected through a resistor 726 to a plus 15-volt power supply, and an emitter electrode 728 connected through a conductor 730 to ground. A base electrode 732 is connected through a conductor to a parallel network 734 of input or current limiting resistors 736 which are connected at the other end thereof to a plurality of input terminals 738. It is to be noted that the preferred norgate is capable of receiving as many as five inputs and due to current carrying capabilities is limited to five. It is to be noted that, by the proper choice of circuit parameters, the number of inputs may be increased. A resistor 740 is interconnected between the base electrode 732 and a negative supply voltage, such as -5 volts, to provide a reverse bias and insure that the transistor 722 is substantially nonconducting when a zero input is present at all input terminals 738.

With a binary zero input, that is, an input of zero to .3 of a volt, at all of the input terminals 738, the transistor 722 is normally nonconductive and an output terminal 742 connected to the collector electrode 724 will read an output voltage of binary one, or approximately 12 to 15 volts, depending on the size of the load being supplied by load terminal 742 connected to the collector. However, if a binary one is impressed on any one or a plurality of the input terminals 738, the transistor will be turned on and current will flow through the collector-emitter circuit to ground. Thus, the collector 724 and the output terminal 742 will immediately drop to a potential which is very nearly ground, and would be approximately .3 of a volt, which is the normal voltage drop across the NPN transistor 722. Thus, with an input of binary one at any input

terminal 738, the transistor 722 will provide an inverted output of binary zero to form a typical negative "or" gate. The symbol for the single gate is indicated as being a triangle with a plurality of five inputs and one output. It is to be understood that any number of input terminals from one to five may be provided.

As stated above, the norgate 720 illustrated in FIGURE 11 is capable of receiving five input signals and in order to multiply the number of input signals which any one norgate module can receive while utilizing the same circuit parameters, it is necessary that a plurality of norgate be connected in parallel. Such a module 744 is illustrated in FIGURE 12, wherein a norgate 720, as described above, is illustrated with the corresponding reference numerals for like components or elements. A second transistor 746 has been added to the circuit with the collector electrode 748 thereof connected in parallel circuit relation with the collector electrode 724 of the transistor 722 and the output terminal 742. As in the above situation, the emitter electrode 750 is connected to ground through a conductor 752 and the base electrode 754 is connected to a second plurality of up to five input terminals 756 through a corresponding number of input resistors 758. In order to provide the positive turnoff stability described above, a resistor 760 is connected at one end to the base circuit 754 and at the other end to a negative voltage, as for example -5 volts.

The output from the paralleled norgates is taken at the common output terminal 742 and, with the connection made as described above, it is seen that any binary one input to any one of the ten input terminals 738, 756 illustrated will produce a binary zero output at the output terminal 742. Limited only by leakage current from base to collector, any number of norgates may be paralleled in the manner described and, with the circuit illustrated in FIGURE 12 the load resistor of the second norgate is eliminated and a common collector resistor 726 is interconnected for both transistors 722, 746. The symbol for the above described norgate module 744 is seen to be a pair of single norgates with their outputs connected to a common terminal and one of the triangles having a dot formed within the periphery thereof.

FIGURE 13 illustrates a current gain means in the form of an emitter follower module 764 which is normally utilized to provide additional driving current for a plurality of driven norgates as a load. Both of the above described norgate modules 720, 744 are capable of driving four norgates, a limitation being placed thereon due to current carrying capabilities of the transistors. Where it is desired that additional norgates be driven, the emitter-follower module 764, such as illustrated in FIGURE 13, has been provided in these situations. The module 764 is capable of driving twelve norgates, thus providing additional driving current to the circuit. The emitter-follower 764 illustrated is of a typical configuration including a transistor 766 having a collector electrode 768 connected to a positive 15 volts through a collector resistor 770. An emitter electrode 772 is connected to ground through an emitter resistor 774, the resistor being of some value considerably higher than the collector resistor 770. A base electrode 776 is connected to an input terminal 778 through a current limiting resistor 780. The transistor 766 is normally in the not conducting state, and an input signal of binary one impressed upon the input terminal will turn the transistor 766 on to the conducting state, thereby providing a binary one at an output terminal 782.

With the transistor 766 in a nonconducting condition, the output terminal 782 connected to the emitter electrode 772 is substantially at ground due to the lack of current flow through the collector-emitter circuit. When the transistor 766 is turned on due to the impression of a binary one signal voltage on the input terminal 778, current will flow from the positive voltage source, through the low value collector resistor, collector-emitter electrodes 768,

772, the high value emitter resistor 774 to ground. Thus the voltage at the emitter electrode 772, to which the output 782 is connected, will rise to a voltage which corresponds supply voltage minus the voltage drop across resistor 770 and the collector-emitter voltage drop. Thus, the output voltage is approximately 12 volts or a binary one at the output terminal 782 and the signal at the output terminal closely follows the signal at the input terminal with a current gain and no inversion of the input signal, as is commonly known in the art. The symbol 784 for the emitter-follower 764 is illustrated as being a circle drawn through the conductor.

Referring now to FIGURE 14, there is illustrated a preferred bistable means in the form of a flip-flop circuit 790, the flip-flop generally comprising a first transistor 792 which is connected by a collector electrode 794 to a source of positive voltage through a collector resistor 796 and the emitter electrode 798 is grounded through a conductor 800 to a ground terminal 802. The collector 794 of the first transistor 792 is connected to a base electrode 806 of a second transistor 808 through a resistor 810 and a conductor 812. The collector 820 of the second transistor 808 is connected to the same source of positive potential by a second collector resistor 822 and the emitter 824 is connected by a conductor 826 to the ground terminal 802. As in the above case, the collector electrode 820 of the second transistor 808 is connected to the base electrode 830 of the first transistor 792 by means of a resistor 832 and a conductor 834. The bases of transistor 792 and transistor 808, respectively, are supplied with a pulsing control signal through a pair of input terminals 840, 842, respectively, which supply input pulses to the base of transistor 792 and the base of transistor 808. A pair of resistors 844, 846 are connected at one end to a negative source of voltage and at the other end to each respective base electrode 838, 806 to provide temperature and operation stability, as described above.

In the operation of the flip-flop circuit, the transistor 792 is normally off or nonconducting and the transistor 808 is normally conducting. When a pulse is fed to the base circuit of transistor 792 through the input terminal 840, the transistor 792 is turned on thereby lowering the voltage at an output terminal 850 which is connected to the collector electrode 794 of transistor 792 to a binary zero output level. This binary zero output signal is also fed to the base 806 of transistor 808 through the resistor 810 and thus lowers the voltage at the base 806 to approximately .3 volt, thereby turning transistor 808 off. It is to be noted that prior to the turning of transistor 792 on, the potential at the collector electrode 794 thereof is substantially at a binary one level. On turning transistor 808 off, the potential at the collector electrode 820 of transistor 808 is raised to substantially 12 volts or a binary one level, thereby feeding a binary one signal to the base of transistor 792 and to an output terminal 852. With the increased constant voltage being fed to base 830, transistor 792 is maintained in the conducting state.

Thus the flip-flop circuit 790 is a bistable device in that a second pulse is needed to revert the flip flop module 790 back to its original state. The output terminal 852 from transistor 808 is connected to the collector electrode 820 by means of a conductor 854, and the resetting pulse for the flip-flop circuit 790 is fed to the other input terminal 842 which is connected to the base electrode 806 through a conductor. Thus in the normal state and the output terminal 850 connected to transistor 792 is at a binary one level, and the output terminal 852 connected to transistor 808 is at the binary zero level. When the flip-flop is to be initially set for operation, a setting pulse of a binary one level is transmitted to the input circuit of the normally conducting transistor or, in the alternative, the input terminal associated with the normally nonconducting transistor is grounded. The flip-flop is reset in a conventional manner by feeding a resetting pulse to one

input terminal or the other, depending on which side of the flip-flop is to be conducting.

Referring now to FIGURE 15, there is illustrated a schematic diagram of a monostable, delayed output pulse forming means in the form of a single shot multivibrator circuit 860. The multivibrator 860 comprises a first transistor 862 having a collector electrode 864 connected to a source of positive potential through a resistor 866 and a blocking diode 868, and the transistor 862 has an emitter electrode 870 which is connected to ground through a conductor 872. A second transistor 878 includes a collector electrode 880 also connected to the same source of positive potential through a resistor 882 and an emitter electrode 884 is connected to ground through a conductor 886. The base electrode 890 of transistor 862 is connected to the collector electrode 880 of transistor 878 through a conductor 892 and a resistor 894 and the base electrode 896 of transistor 878 is connected to the collector electrode 864 of transistor 862 through a blocking diode 904 and a capacitor 906, for a purpose to be hereinafter explained.

The junction of the connection between the capacitor 906 and diode 904 is connected to the positive source of potential through a resistor 910 to provide a base-emitter circuit for the normally conducting transistor 878. The resistor 866 and diode 868 provide a current path in parallel with resistor 910 to charge capacitor 906 during the period current is flowing therethrough to the base-emitter circuit transistor 878. The diode 904 serves to protect the base-emitter circuit of transistor 878 from a high voltage which may appear thereacross due to the charging and discharging operation of capacitor 906, as will be seen from the following description. The base electrodes 890, 896 of both transistors 862 and transistor 878, respectively, are also connected to a negative source of potential through a first resistor 916 and a second resistor 918, respectively, to provide positive turn-off and temperature stability. The input to transistor 862 is provided through an input terminal 920 which is connected to the base electrode 890 by means of a conductor 922 and the input to transistor 878 is provided through an input terminal 924 which is connected to the base electrode 896 by a second conductor 926.

In the operation of the device, transistor 862 is normally nonconducting and transistor 878 is normally conducting thereby providing a binary one output at an output terminal 930 connected to the collector electrode 864 and a binary zero at an output terminal 932 connected to collector electrode 880. The main current flow through transistor 878 is from the positive potential source through the resistor 882, the collector-emitter electrodes of transistor 878 to ground. When an input pulse is impressed on input terminal 920, transistor 870 begins to conduct through resistor 866, diode 868, the collector-emitter electrodes of transistor 862, conductor 872 to ground. Prior to the conduction of transistor 862, the capacitor 906 is charged by the voltage drop across resistor 910, the potential of which is applied to the series combination of resistor 866, diode 868 and capacitor 906. The drop across resistor 910 is provided by the base-emitter current of transistor 878 and the resistor 866 forms the resistance portion of the RC charging circuit.

Thus the capacitor is charged to a predetermined potential, the time constant of which is determined by the resistor-capacitor combination 866, 906. The charging potential of capacitor 906 is continued until such time as the transistor 862 is turned on by a positive trigger pulse from input terminal 920 or when the capacitor 906 is fully charged. The conduction of transistor 862 discharges the capacitor 906 through resistor 910 and the emitter collector circuit of transistor 862 thereby lowering the potential at node 909 and placing a back biasing voltage on the emitter-base circuit of transistor 878 to turn the transistor 878 off. The diode 904 is included in the circuit to provide protection of the emitter-base circuit of transis-

sistor 878 from this reverse voltage. The time of discharge of the capacitor 906 is determined by the resistor 910 connected to the positive source of potential and the impedance of transistor 862.

With the back biasing of the diode 904 in the transistor 878 base circuit, the transistor 878 is turned off and an output pulse of a binary one will result at the output terminal 932 connected to the collector of transistor 878. This output pulse will have a duration which is determined by the RC time constant of the capacitor discharge circuit and at such time as the capacitor is discharged sufficiently, the reverse bias will be removed from the diode 904, the transistor 878 will turn on and as a result the transistor 862 will turn off again. The subsequent turning off of transistor 862 is due to the dropping of the potential at the collector 880, which potential is fed to base 890 through resistor 894. Thus a substantially square wave pulse of specified duration is produced. It is to be noted that a negative trigger pulse may be fed to the input terminal 924 connected to transistor 878 and achieve the same results. The symbol to be used hereinafter to indicate a single shot multivibrator is indicated at 938.

Referring now to FIGURE 16, there is illustrated a flip-flop module 950 having a diode steering network incorporated therein. The flip-flop comprises a pair of transistors 952, 954 connected in a manner similar to that described in conjunction with FIGURE 14, wherein transistor 952 has a collector electrode 956 connected to a positive source of potential through a resistor 958 and an emitter electrode 960 connected to ground by means of a conductor 962. The collector electrode 966 of transistor 954 is connected to the same source of positive potential by means of a resistor 968 and the emitter electrode 970 is connected to ground through a conductor 972. The base of transistor 952 is connected to the collector 966 of transistor 954 by means of a conductor 974 and a parallel circuit combination 976 of a resistor and a capacitor, the capacitor being utilized in this case to speed up the response time of the flip-flop unit. Similarly, the base electrode of transistor 954 is connected to the collector electrode 956 of transistor 952 by means of a conductor 980 and a parallel circuit combination 982 of a resistor and a capacitor, the capacitor being for the same speed up purpose as in the above case. Temperature stabilization and positive cutoff is provided by means of a pair of resistors 984 and 986 connected to a negative potential, as was described above. The input to transistor 952 is provided through the connection to the base 988 thereof of a resistor 990, capacitor 991, and diode 992 while the input to transistor 954 is supplied through the resistor 990 and a second capacitor 993 and diode 994 connected to base 989.

The input circuit is connected to ground through a resistor 995 to provide a discharge path for the capacitors 991, 993. The collector voltage for transistor 952 is fed to the cathode of diode 992 through a high value resistor 996 connected at one end to collector 956 and at the other end to diode 992. Similarly, transistor 954 has a like circuit wherein a high value resistor 997 is connected to the collector electrode 966 of transistor 954, and the other end of resistor 997 is connected to the anode of diode 994, for a purpose to be explained. The input pulse to the base electrodes 988, 989, is provided to the juncture between the capacitors 991, 993 by means of an input terminal 998 and the resistor 990. The outputs of the flip flop circuit are taken from terminals connected to the respective collector electrodes of the two transistors. If one output pulse is desired for every two input pulses, the output is derived from one collector electrode or the other, or if the true and false outputs are required, the output signal is derived from both collector electrodes. In the latter situation, a single input pulse will switch the output pulses from one collector electrode to the other. The symbol for this module is indicated at 999 wherein is illustrated the single input terminal and two output terminals.

In operation, and assuming that the transistor 952 is nonconducting and transistor 954 is conducting, a positive voltage of approximately 12 volts will appear at the collector electrode 956 of transistor 952. This voltage being fed to the cathode of diode 992 through resistor 996. This 12-volt potential is also fed to the base electrode 989 of transistor 954 by means of resistor-capacitor combination 982 and conductor 980. Thus, transistor 954 will be maintained in the conducting condition. Under these conditions the voltage at the base electrode 989 is normally approximately .8 of a volt and the voltage at the base 988 of transistor 952 is normally at negative reverse bias voltage, this voltage being fed from the drop produced by resistor-capacitor circuit 976 and resistor 984 which is connected to a 5-volt supply. Also the potential at collector 966 is fed to the cathode of diode 994 by means of resistor 997 thereby putting approximately a .3 of a volt potential at the cathode which will put diode 994 in the conduction state. When a positive pulse is fed to terminal 998, a positive and negative spike will be fed to the cathodes of both diodes 992 and 994. With diode 992 being greatly back biased by the positive 12 volt potential being fed to its cathode, no effect will be realized on transistor 952. However, the negative going spike will greatly forwardly bias diode 994 due to the fact that the spike is approximately a negative 12 volts as compared to the +.8 of a volt at its anode. Thus the potential being fed to the base 989 from cathode 994 is shunted to ground and the transistor 954 is turned off. With the turning off of transistor 954 the base electrode 988 of transistor 952 is raised to the +12-volt potential through resistor-capacitor circuit 976. Accordingly, transistor 952 is turned on and a binary zero output is realized at its collector electrode 956. When a second pulse is impressed on the input terminal 998, the transistor 952 will be effected in that the conditions described above will be exactly reversed for each of the transistors 952 and 954. Thus, with the second pulse, the transistor 952 will be turned off and, as a result, transistor 954 will be turned on.

Referring now to FIGURE 17, there is illustrated a transistorized driver circuit 1000 which is utilized to provide additional driving current for certain coils and other inductive load portions of the system to be described. In the driver circuit 1000, an NPN transistor 1002 having a collector electrode 1004 connected to a source of positive potential through a load (not shown), such as an operating coil of the typewriter 75, through a pair of conductors 1006, 1008 and has an emitter electrode 1010 which is grounded by means of a conductor 1012. An input pulse to the circuit is fed by means of input terminal 1014 to a base electrode 1016 of the transistor through a resistor 1018. A temperature stabilizing resistor 1020 is connected from a source of negative potential to the base electrode 1016. The load device is connected in series circuit with the collector-emitter electrodes and the current through the load is controlled by the transistor 1002. Thus, as an input signal is fed to the base, the normally nonconducting transistor is switched to the conducting state and a large amount of current is drawn through the load circuit and the collector-emitter circuit of the transistor. In this way the input current signal is amplified to provide a high load current as would be required in the case of a solenoid coil load. The symbol for the driver circuit 1000 is illustrated at 1018.

FIGURE 18a illustrates a typical coupling circuit means 1022 which is utilized to couple a positive pulse to a pulse receiving circuit. In the coupling circuit 1022, a capacitor 1024 and a diode 1026 are connected in series circuit between an input terminal 1028 and an output terminal 1030 by means of a conductor 1032. A resistor 1034 is connected to the conductor 1032 at one end thereof and to ground at the other end thus providing the conventional RC coupling with a blocking diode. The resistor 1034 allows the capacitor 1024 to discharge through ground 70 to reset for the next pulse. A typical output pulse is illus-

trated in FIGURE 18a with the symbol for the coupling circuit illustrated at 1036.

FIGURE 18b illustrates a coupling circuit means 1040 which is adapted to be utilized with a negative input pulse. In this situation the capacitor 1024 and diode 1026 are connected between the input and output terminals by means of the conductor 1032. However, the diode 1026 is reversed in polarity from the situation described in conjunction with circuit FIGURE 18b, thus allowing the negative spike to pass to the output terminal 1030 and blocking the positive spike. As in FIGURE 18a the resistor 1034 is connected between a grounding circuit and the conductor 1032 to form a discharge path for the capacitor 1024. The symbol of this network is illustrated at 1042.

FIGURE 19 illustrates a preferred grounding circuit 1048 which is utilized to ground certain signals which are generated in the system to be described. In the grounding circuit 1048, an NPN transistor 1050 is connected between the conductor 1052 carrying the signal to be grounded by means of its collector electrode 1054 and an emitter electrode 1056 is connected to ground through a conductor 1058. An input signal to the NPN transistor 1050 is provided through an input terminal 1060 which is connected to a base electrode 1062 by means of a current limit resistor 1064. A cutoff resistor 1066 is connected at one end thereof to the base electrode 1062 and at the other end to a source of negative potential, as for example, negative 5 volts. In operation, when it is desired to ground a certain signal, an input pulse is fed to the input terminal 1060 thus turning the normally nonconducting transistor 1050 to the conducting state, thereby substantially grounding the input terminal 1052 connected to the collector electrode 1054. Thus any conductor connected to the input will be immediately dropped to ground or +.3 of a volt potential. The symbol for the grounding circuit 1048 is illustrated at 1068.

READER AND TYPEWRITER INPUT LOGIC CIRCUITS

Referring now to FIGURES 20 to 22 and the left portion of FIGURE 23, there is illustrated the reader input logic section, corresponding to the reader input logic 574 of FIGURE 10. As described above, the eight outputs from the reader unit 77 are fed to the input flip flop section 612 and these outputs are in turn impressed on the logic circuit 616. While the system to be described does not utilize the full capability of an eight channel system, the eight channel system will be described as a typical example of the utilization of principles in the present invention as stated above.

The reader unit 77 produces a plurality of electrical signals which are generated by means of the solar cells 390-404 described above, these electrical signals being fed to eight input terminals 1080 to 1094 of the reader input logic section. A plurality of secondary input terminals 1096 are provided to permit the receive of signals from an auxiliary reader unit. The input signals from either reader unit are of the order of a plus 12 volts, or a binary one level. The reader input flip flop section 1098 is divided into three portions, 1098a, 1098b, and 1098c, the first 1098a of which is responsive to the first three channels of the reader comprising the first three bits of information produced by the reader unit, the second is responsive to channels four, five and six corresponding to the fourth, fifth and sixth bits of information and the third section is responsive to channels seven and eight corresponding to the seventh and eighth bits. This configuration of sectionalizing the eight channels of the reader input flip-flop section 1098 provides the most effective use of the eight channels with a minimum of circuit elements in the situation where the full capacity of the system is not being utilized. When a binary zero output is produced at any one of a plurality of output terminals

1100-1107, it indicates that that particular configuration of bits, corresponding to the respective channels has been read and all of the other output terminals in any one section will be at a binary one. Similarly, in the second and third sections, one set of output terminals 1108-1115 and 1116-1119, respectively, in each will be at a binary zero and all other sections will be at a binary one level output signal.

Thus, for any particular configuration of input signals, a binary zero will appear in one, two and three bit section 1098a, a second binary zero will appear in the four, five and six bit section 1098b, and a third binary zero will appear in the seventh and eighth bit section 1098c. This is obvious when it is realized that each of the sections has an output terminal which signals the lack of a bit punched in each of the channels of the particular section, 1098a, 1098b, and 1098c. By way of example, if channel one has been punched and the other channels in the particular column of the tape have not been punched, a binary zero output would be impressed on output terminals 1101 in section 1098a, a binary zero would be present on terminals 1108 in section 1098b and a binary zero at terminals 1116 in section 1098c. Terminals 1101 correspond to a one, not two and not three, symbolized 123, terminals 1108 to not four, not five and not six, symbolized 456 and 1116 to a reading of not seven and not eight symbolized 78. All of the other output terminals of the group 1100 to 1119 will be at a binary one level, as will be hereinafter explained.

The input flip-flop logic section 1098 generally comprises a plurality of flip-flop units 1120-1134 corresponding to each of the eight input channels wherein the set side of the flip-flop unit is normally at a binary one output and the reset side of the flip-flop is normally at a binary zero output. For purposes of this description, the side of the flip-flop circuit to which an information or other signal is fed, thereby switching the flip-flop to its opposite state from the normal conditions, will be referred to as the "set" side. On the other hand, the side to which the pulse is fed to effect a switching of the flip-flop back to its normal state will be referred to as the "reset" side. The first section 1098a contains three flip-flop units 1120, 1122, 1124 corresponding to the three bit inputs and by considering the formula of 2^n , where n is the number of units being actuated, it is seen that the formula yields a two to the third power, or eight possible combinations of the three input bits. Thus it is necessary that eight sets of output terminals be provided in order that all of the possible combinations of the three input bits are considered. Thus a plurality of eight norgates 1140-1154 have been provided and the set and reset side outputs of the flip-flop units 1120, 1122, 1124 are interconnected with each of the eight norgates 1140-1154. Taking the first flip-flop unit 1120 and first considering the set side 1156, which is normally at a binary one output when it has not been pulsed, the input signal from terminal 1080 is impressed on the set side 1156 by means of an RC coupling circuit 1158. The set side 1156 is connected to the norgate 1142 by means of conductors 1160, 1162, 1164. The set side 1156 is also connected to the norgate 1146 by means of the conductor 1162 and another conductor 1166 and to the gates 1150, 1154 through conductor 1162 and a conductor 1168. The reset side 1170, or normally binary zero side, of the flip-flop unit 1120 is connected to norgate 1144 by means of a conductor 1172 and another conductor 1174. It is also connected to the norgate 1140 through conductor 1172, to the norgate 1148 by conductor 1172 and a conductor 1176 and the norgate 1152 by conductor 1172. Thus, with flip-flop unit 1120 in its normal condition, the norgates 1142, 1146, 1150, 1154 will have a binary one input on the respective input conductors, and norgates 1140, 1144, 1148, 1152 will have a binary zero on the respective input conductors.

The second flip-flop unit 1122, corresponding to a read-

ing in the channel two position, has its set side 1178 connected to norgate 1144 by means of conductors 1180, 1182 and is also connected to norgate 1146 by the conductors 1180, 1182 and a conductor 1184. The set side 1178 is also connected to norgate 1152 by conductors 1182 and 1186, and to 1154 by the conductor 1182. The reset side 1188 is connected to norgates 1140, 1142, 1148, 1150 by means of a plurality of conductors 1190, 1192, 1194 and 1196. Similarly, the third flip-flop unit 1124 has its set side 1282 connected to the norgates 1148, 1150, 1152, 1154 and the reset side 1284 is connected to the norgates 1140, 1142, 1144, 1146.

The output of norgate 1140 is fed to a single input inverter gate 1200 by means of a conductor 1202 which inverts the input signal from a binary one to a binary zero level, or vice versa, and subsequently feeds the output signal of the gate 1200 by means of conductors 1204 and 1206 to a pair of emitter followers 1208, 1210, respectively, the emitter follows 1208, 1210 amplifying the current signal without inverting the polarity thereof. The respective outputs of the emitter followers 1208, 1210 are fed to the output hubs 1100 by means of conductors 1212 and 1214, respectively. Thus, output hubs 1100 are responsive to a sensing of a lack of punched holes in channels one, two and three and thus give an output reading of not one, not two and not three ($\bar{1}\bar{2}\bar{3}$), as specifically indicated on the drawing. Similarly, the output of norgate 1142 is fed to an inverter gate 1220, which inverts the input signal and impresses its output through a pair of conductors 1222 and 1224 to a pair of emitter followers 1226, 1228. As in the above situation, the emitter followers 1226, 1228 amplify the current signal without inversion thereof and impresses the output on output hubs 1101 by means of a pair of conductors. These output hubs are responsive to a reading of a binary one signal in channel one with a binary zero in channels two and three. Thus, this output is responsive to a one, not two and not three ($\bar{1}\bar{2}\bar{3}$).

The output from norgate 1144 is fed to an inverter gate 1230 by means of an output conductor and the output of gate 1230 is fed to a pair of emitter followers 1232 and 1234 by means of conductors 1236, and the outputs of the emitter followers 1232, 1234 are fed to the output hubs 1102 by means of a pair of conductors 1238. These output hubs are responsive to a signal corresponding to a not one, two and not three ($\bar{1}\bar{2}\bar{3}$). Further, the output of norgate 1146 is fed to inverter gate 1240 which in turn is fed to the output hubs 1103 through emitter followers 1242, 1244 which correspond to a combination of one, two and not three ($\bar{1}\bar{2}\bar{3}$). Similarly, norgate 1148 is connected to inverter gate 1250 with its respective emitter followers 1252, 1254 and output terminals 1104, norgate 1150 is connected to inverter gate 1260 with its respective emitter followers 1262, 1264 and output terminals 1105; and norgate 1152 is connected to inverter gate 1270 with its respective emitter followers 1272, 1274 connected to output terminals 1106. Lastly, the norgate 1154 is connected to an inverter gate 1276 and thence to the output terminals 1107 by means of a pair of emitter followers 1278 and 1280. The notation of the combinations being indicated by the output terminals 1100 to 1107 is indicated to the right of the respective output hubs.

In operation and assuming that a binary one signal is received from the reader unit 77 corresponding to a punching in channels one and three, the following description is an indication of the operation of the one, two and three bit section and it is to be understood that this operation is identical for the four, five and six bit section, and the seven and eight bit sections. When a binary one signal is received at the channel one input terminal, the flip-flop unit 1120 is switched from a binary one output on its set side 1156 to a binary zero output and its reset side 1170 is switched from a binary zero to a binary one. The binary zero signal from its set side 1156 is fed to the corresponding norgates 1142, 1146, 1150, 1154 and the binary one

from its reset side 1170 is fed to norgates 1140, 1144, 1148 and 1152. With a binary one on any input terminal of a norgate, the output thereof will be a binary zero, thus a binary zero output will be fed to gates 1200, 1230, 1250, 1270 to give a binary one at output terminals corresponding to not one, not two and not three ($\bar{1}\bar{2}\bar{3}$), not one, two and not three ($\bar{1}\bar{2}\bar{3}$), not one not two and three ($\bar{1}\bar{2}\bar{3}$), and not one, two and three ($\bar{1}\bar{2}\bar{3}$).

Turning now to the flip-flop unit 1122, corresponding to the input from channel two, which received a binary zero signal at the input terminal 1082 due to the channel not being punched or read, the flip-flop 1122 will remain at its normal state of binary one on the set side 1178 output and a binary zero on the reset side 1188 output. The binary one on the set side 1178 is fed to norgate 1144 which has had a binary one placed on its input due to the reset side signal of flip-flop 1120. Also the binary one signal is fed to the norgate 1146 which places a binary zero on its output terminal, this signal being fed to gate 1240. The gate 1240 then inverts the input signal to give a binary one at the output terminals 1103, corresponding to a one, two and not three. Also the binary one from the set side of 1188 of flip-flop 1122 is fed to norgate 1148, which had a binary one at its input in accordance with the binary one fed there by the reset side 1170 of flip-flop 1120, thus producing a binary one output at terminals 1104. However, the binary one is also fed to norgate 1154 which produces a binary zero input to gate 1276 which is fed in turn to output terminals 1107 corresponding to a reading of one, two and three. The reset side 1188, having a binary zero signal on its output, supplies a binary zero to norgate 1140 and the norgates 1142, 1148, which had a binary one impressed on the input terminals thereof, and the binary zero is also fed to gate 1150. Thus two binary zero inputs are impressed on the first and third input leads to norgate 1150.

The third flip-flop unit 1124 receives a binary one input signal which switches its set side to a binary zero output and binary one output at the reset side. The binary zero output is fed to norgate 1154 which has been fed a binary one input, to gate 1152 which similarly has a binary one input, to gate 1150 at its middle input lead and to gate 1148 which had a binary one input previously impressed thereon. The binary one from the reset side is fed to norgates 1146, 1144, 1142, this latter norgate 1142 having its output signal inverted by norgate 1220 which then inputs the binary one signal to emitter followers 1226, 1228 to give a binary one output at the output hubs 1101 corresponding to a one, not two and not three. Also, the binary one from flip-flop 1124 is fed to norgate 1140 which gives a binary one output at output hubs 1100 corresponding to a not one, not two and not three.

Thus, with three binary zero signals existing at the input to norgate 1150, the output of the gate is ready to switch to a binary one output signal, this binary one signal is fed to gate 1260 which will correspond to a reading in channels one and three. However, the fourth input lead to all of the gates carries a binary one signal thereon, which remains on that input lead at all times except when a strobe signal is generated from the reader control circuit, as will be hereinafter explained. In order to fully understand the operation of this portion of the circuit, it is assumed that the strobe signal takes the normally existing binary one signal at the fourth input leads and grounds it to zero, thereby removing the inhibit from all of the output norgates. This strobe signal is synchronized with the operation of the reader unit 77 to insure that all of the required information has been fed to the norgates 1140 to 1154 and further insures that all of the information is read simultaneously. Thus, the chance of spurious signals entering the system is greatly reduced and the system is synchronized. This strobe signal is fed by means of a conductor 1286 to strobe the top ten norgates and the other norgates illustrated in FIGURE 21 and 22 are strobed by a further signal which has been amplified by

an emitter follower arrangement, to be hereinafter explained. Thus, when the signal level on the fourth input lead to norgate 1150 drops to a binary zero, the output terminal thereof will rise to a binary one level. This output signal is inverted by means of gate 1260 to give a binary zero output at output hubs 1105, corresponding to a reading of one, not two and three at the reader unit. It is to be noted that all of the other output hubs are at a binary one with the exception of the foregoing output hubs 1105, corresponding to one, not two and three.

Referring now to FIGURE 21, it is seen that the four, five and six bit section 1098b includes identical connections between the flip-flop unit 1126 for channel four, flip-flop unit 1128 for channel five, flip-flop unit 1130 for channel six and a plurality of norgates 1290 to 1304 as described in conjunction with the one, two and three bit section. The input signal to flip-flop 1126 is provided by an input terminal 1086 connected to channel four and an RC coupling circuit 1306 and, as in the above situation, the flip-flop 1126 normally is at a binary one on its set side 1310 and a binary zero on its reset side 1312. The set side 1310 of flip-flop 1126 is connected to a plurality of norgates 1292, 1296, 1300 and 1304, and the reset side 1312 is connected to a plurality of norgates 1290, 1294, 1298 and 1302. The input to flip-flop unit 1128 is provided by the input terminal 1088 through the positive coupling circuit 1316 and the set side 1318 is connected to norgates 1294, 1296, 1302 and 1304 and the reset side 1320 is connected to norgates 1290, 1292, 1298 and 1300. The input from channel six is fed to the input terminal 1090 and accordingly fed to flip-flop 1130 through a coupling network 1322. The set side 1326 is connected to norgates 1298, 1300, 1302 and 1304 and the reset side 1328 is connected to norgates 1290, 1292, 1294 and 1296. It is to be noted that the norgates 1290 and 1292 are strobed through the same conductor 1286 and signal that was described in conjunction with the one, two three bit section, and the strobe signal for the lower norgates 1294 to 1304 is provided through a second strobe conductor 1451 for the reason described above.

The output from norgate 1290 is fed to an inverter gate 1332 by means of a conductor 1334 and the inverted signal is fed to output hubs 1108 through emitter followers 1336 and 1338 wherein the output hubs correspond a reading of not four, not five and not six. The output from norgate 1292 is fed to an inverter gate 1340 by means of a conductor 1342 and this output is fed to output hubs 1109 corresponding to four, not five and not six through emitter follower circuits 1352 and 1354. The output from norgate 1294 is fed to an inverter gate 1350, the output of which is fed to output hubs 1110 corresponding to not four, five and not six by means of emitter followers 1342 and 1344.

The output from norgate 1296 is fed to inverter gate 1358 and in turn is fed to output hubs 1111 corresponding four, five and not six through emitter followers 1360 and 1362. Norgate 1298 is connected to inverter gate 1366 and in turn to output hubs 1112 corresponding to not four, not five and six, through emitter followers 1368, 1370. Norgate 1300 is connected to norgate 1374 and in turn to output hubs 1113 corresponding to four, not five and six through emitter followers 1376 and 1378. Similarly, norgate 1302 is connected to a norgate 1384 and norgate 1304 is connected to a norgate 1386 and correspondingly to output hubs 1114, 1115, respectively, corresponding to not four, five and six, and four, five and six through emitter followers 1390, 1392 and 1394, 1396, respectively.

Turning now to the section corresponding to channels seven and eight in FIGURE 22, it is seen that flip-flop 1132 is connected to the input terminal 1092 for channel seven through a coupling circuit 1400 and the output of the set side 1402 thereof is connected to a norgate 1404 and a norgate 1406, and the reset side 1408 is connected to norgates 1410 and 1412. The input for channel eight

is impressed on the input terminal 1094 and consequently fed to the set side 1418 of flip flop unit 1134 by means of a coupling circuit 1420. The output of the set side 1418 is fed to norgates 1412 and 1406 and the reset side 1422 is fed to norgates 1404 and 1410. The output from norgate 1410 is fed to inverter gate 1430 and in turn is fed to the output hubs 1116 corresponding to a not seven and not eight by means of a plurality of emitter followers 1432. The additional emitter followers are provided in this section to provide additional current in certain applications wherein channel seven and eight outputs are provided. In this situation the power is needed for sixty-four gates, which is not the situation wherein only the first six channels are being used. Similarly, Norgate 1404 is connected to inverter gate 1434 and to output hubs 1117, corresponding to seven and not eight, by means of a plurality of emitter followers 1436. Also, the outputs of norgates 1412 and 1406 are fed to inverter gates 1440 and 1442, respectively, through emitter followers 1446, 1448, and in turn to output hubs 1118 and 1119 corresponding to not seven and eight, and seven and eight, respectively. As in the above situation, when channels seven and eight are not being read or are not punched, all of the output hubs in this section with the exception of the output hubs 1116 corresponding to not seven and not eight will be at a binary one level whereas the hubs 1116 will be at a binary zero level.

The strobe signal for this section is provided through conductor 1454 to emitter follower 1450 connected to a conductor 1451, this signal being fed to the lower section of the four, five and six bit section of FIGURE 21. The strobe signal being fed to the upper ten gates of FIGURES 20 and 21 is carried by conductor 1454 and amplified by an emitter follower 1458 connected to conductor 1286. Also, conductor 1454 provided a reset signal for each of the flip-flop units 1120 to 1134, both the strobe and reset signals being derived from a source to be hereinafter explained. The reset signal is fed to the flip-flop units corresponding to channels one to eight to provide the reset signal to the reset sides of all of the flip-flop units. Thus, the input signal sets the respective flip-flop units 1120-1134 and the output norgate have the input signals stabilized when the strobe signal occurs. Upon completion of the strobe signal, the flip-flop 1120-1134 are reset and the strobe signal will not occur until the reader control circuit has generated the next strobe signal, as will be explained in conjunction with the reader control circuit.

Each of the signals on the set sides of each one of the 50 flip-flops corresponding to the eight channels, is fed to a second plurality of norgates 1460 to 1474 having three input terminals, one of which is connected to each of the corresponding outputs of the set side of each one of the flip-flop units described above by means of a plurality of conductors 1478. A plurality of output hubs 1480 associated with each of the norgates are connected to a non-print section of the punch portion, as will be hereinafter described. In addition to the eight channels, a binary zero norgate 1484 is provided, the inputs 1485, 1486, 1487 of 55 which are connected to the not one, not two and not three hubs 1100, the not four, not five and not six, hubs 1108, and the not seven and not eight hubs 1116. Thus, when none of the channels have been read, a binary one will be present on the binary zero output hub 1482 of norgate 1484 for a purpose to be hereinafter explained. An inhibit 60 signal is also placed on the norgates by means of a conductor 1488 which has a constant binary one signal level present until such time as the nonprint outputs are desired to be used. This function will be explained in conjunction with certain other figures of the drawings. Also, the strobe signal being supplied by conductor 1454 also provides a strobe signal for gates 1460 to 1484 through emitter follower 1490 and conductor 1492.

Thus, the signals from the eight input channels are 65 fed through logic circuitry to output hubs 1100 to 1119

which provide twenty output signals corresponding to eight output signals for the one, two and three bit section, eight output signals for the four, five and six bit section, and four output signals corresponding to the seven and eight bit sections. It is to be noted that since the logic of the three sections are not interconnected, all of the possible combinations of the eight channels are not being utilized insofar as the two hundred fifty-six signals are not required for the operation of a typewriter or punch tape unit. As will be seen as the description proceeds, the typewriter needs forty-four character signals corresponding to the letters and a certain number of machine function signals which provide a signal for performing certain machine functions, such as carriage return, tab, back space, upper shift, lower shift, etc.

Referring now to FIGURE 23 there is illustrated the remainder of the reader input logic and the complete typewriter input logic circuits. In this figure, the output of each of the hubs 1100 to 1119, corresponding to the one to eight bit sections 1098a, 1098b, 1098c, are fed to a plurality of input hubs 1500, the two sets of hubs 1100 to 1119 and 1500 being interconnected according to a particular schedule of programming.

For purposes of simplicity, only a portion of the wiring and input hubs will be specifically described, and it is to be understood that the hubs 1500 are wired to the output hubs 1100 to 1119 in accordance with the program of typewriter interposer codes indicated to the left of FIGURE 23. For example, an input hub 1500, indicated as corresponding to a reading of 1456 will be connected to output hubs 1101, corresponding to one, not two and not three, 1115 corresponding to four, five, six and 1116 corresponding to not seven and not eight. In the instant situation, a certain portion of the twenty sets of output hubs 1100 to 1119 are provided for the forty-four characters and a further number of the hubs 1100 to 1119 are provided for the machine functions circuit. Referring now to the input section of the circuit 1498, forty-four norgates are illustrated, 1501 to 1544 and it is seen that each of the norgates are provided with three input conductors connected to the input hubs 1500. The three hubs are adapted to be connected to three of the output hubs 1100 to 1119, one in each of the sections 1098a, 1098b, 1098c, described above.

The foregoing description of the reader input logic section is predicated on the fact that any type of code may be utilized to initially encode the tape being fed through the reader unit. As is well known, there are many and various types of codes being utilized in systems of this type, and it is contemplated that any of these codes may be utilized in the reader unit and the code may be made compatible with the rest of the system by properly programming the interconnections between output hubs 1100 to 1119 and input hubs 1500. Also, the typewriter unit may be of a particular code arrangement which may or may not be different from the code being utilized on the reader section. These codes vary from machine to machine and vary in accordance with the position of the keys on the particular typewriter unit itself. In any particular instance the typewriter machine may have a particular key designated for a particular letter and when this key is actuated, a particular sequence of bails within the machine are actuated. Also, on the input side of the typewriter unit, a particular letter or character may energize a particular sequence of interposers to print that particular character. With the system of the present invention, it is contemplated that by proper interconnection of the reader input logic section and the typewriter input logic section, any code may be utilized in the reader section and be made compatible with the code being utilized in the typewriter section.

Thus, a paper tape encoded on a punch unit and typewriter unit of one manufacturer and utilizing one particular code, may be utilized to actuate a typewriter unit of another manufacturer utilizing another code with the

resulting tape. This compatibility of the system is accomplished by proper interconnections between the reader logic section and the typewriter logic section. Similarly, the codes being utilized in the reader section to activate a particular machine function may not correspond to the code of the typewriter unit itself and a similar compatibility problem exists. Accordingly, by proper interconnections between the reader section and the typewriter function input section, the codes of the two sections may be made compatible for any code being used in either of the units.

Assuming as an example in the above described situation that one of the input hubs 1500, as for example the top hub to gate 1501, will be wired to an output hub 1100 to 1107 in the one, two and three bit section, the second hub of gate 1501 will be wired to an output hub 1108 to 1115 of four, five and six bit section, and the third input hub of gate 1501 will be wired to an output hub 1116 to 1119 of the seven and eight bit section. As was stated above, each of the three sections will have one, and only one, output that is a binary zero and all of the other hubs will have a binary one output thereon. Accordingly, a certain three output hubs 1100 to 1119 going to one of the norgates 1501 to 1544 in this section will have all zeros on the input which correspond to a zero from each one of the bit sections. Looking at the first norgate 1501 and observing that an output of binary one at its output terminal will represent a reading of channel one, channel two, channel three, channel four and channel five as noted to the left of the figure, it is seen that the first input hub 1500 of gate 1501 will be connected to the one, two and three output hub 1107 of the one, two and three bit sections. The second input hub of gate 1501 will be connected to the four, five and not six output hub 1111 of the four, five and six bit section, and the third input hub of gate 1501 will be connected to the not seven and not eight output hub 1116 of the seven and eight bit section.

Similarly, the rest of the forty-four sets of three input hubs 1500 will be provided with a conductor from one of each of the sections 1098a, 1098b, and 1098c to any one norgate of the group 1501 to 1544. With the foregoing signals received at the inputs to gates 1501 to 1544, the outputs of gates 1502 to 1544 will be at a binary zero level and the output of gate 1501 will be at a binary one level due to the binary zero level inputs at all of its input terminals. The outputs of the norgates 1501 to 1540 corresponding to the coded input signals being fed to input hubs 1500 are fed by means of a plurality of sets of conductors 1550 to 1568 to a plurality of ten norgates 1570 to 1588. It will be observed that the input gates have been arranged in groups having a common factor in the input signals being fed thereto. For example, the first four gates have a common factor of channels one, two, three and four, the next four of channels two, three and four, the next of channels one, three and four, the next of three and four and so forth for readings of channels one and four, one, two and three, two and three, one and three, three and one. Each of these combinations have been included with the various combinations of five, six, five and six, and not five and not six.

The gates 1501 to 1540 having a channel five and six influence on the input terminals thereof also have their outputs fed to a ten input norgate 1590 by means of a plurality of ten conductors 1592. Thus the outputs of gates 1503, 1507, 1511, 1515, 1519, 1523, 1527, 1531, 1535 and 1539 are fed to the input terminals of gate 1590 by means of the conductors 1592. Similarly, the outputs of these gates 1501 to 1540 having a channel six signal and not channel five are fed to a second ten input norgate 1596 by means of a plurality of conductors 1598. Accordingly, the outputs of gates 1502, 1506, 1510, 1514, 1518, 1522, 1526, 1530, 1534 and 1538 are fed to the input terminals of norgate 1596 by means of the conductors 1598. The same situation occurs for those gates 1501, 1505, 1509, 1513, 1517, 1521, 1525, 1529, 1533 and 1537

having a reading of channel five on their input terminals. The outputs of these latter gates are fed to a third ten input gate 1600 by means of a plurality of conductors 1602. Thus, each time an input gate 1501 to 1540 senses channels five and six, a channel six or a channel five, an output is fed to one of the gates 1570 to 1588 and also to one of the gates 1590, 1596 or 1600 by means of conductors 1550 to 1568 and 1592, 1598, 1602 respectively. The outputs of gates 1590, 1596, 1600 are inverted by a plurality of inverter gates 1604, 1606, 1608.

The outputs of norgates 1570 to 1588 are fed to a plurality of single input inverter gates 1610 to 1628 which invert the signal and provide a binary one at the output terminals thereof at such time as a particular gate 1570 to 1588 has been actuated by a binary one signal impressed at the input terminals thereof. The outputs of gates 1610 to 1628 are in controlling relation with and are utilized to actuate a plurality of four interposer means 1632, 1634, 1636, 1638 by means of a logic network 1640. As illustrated, the output of gate 1610 is fed to a plurality of norgates 1650, 1652, 1654, 1656 by means of an output conductor 1658 and the output of gate 1612 is fed to gates 1652, 1654, 1656 by an output conductor 1660. Similarly, the outputs of gates 1614 to 1628 are impressed on the inputs of gates 1650, 1654, and 1656, 1654, and 1656, 1650 and 1656, 1650, 1652 and 1654, 1652 and 1654, 1650 and 1654, 1654, and 1650, respectively, by means of conductors 1662 to 1676, respectively. The particular groupings of the inputs to gates 1570 to 1588 is related to the common factors described above wherein the first four gates 1501 to 1504 are connected to gate 1570 to provide an output at interposers one to four in accordance with the common factor of channels one, two, three and four. The other gates 1505 to 1540 are similarly grouped in their connection to the respective gates 1572 to 1588.

A binary one on any or all of the input terminals to gates 1650 to 1656 will produce a binary zero output level at the respective output terminals which is, in turn, fed to a plurality of inverter gates 1682 to 1688. The signal is inverted by these latter gates 1682 to 1688 and impressed on a plurality of driver circuits 1692 to 1698 by means of conductors 1702 to 1708, thereby raising the current level of the signal. The coils of the interposers are in series circuit with the collector-emitter circuit of the transistors contained in driver circuits 1692 to 1698 to energize the coils each time a binary one level signal is received at the inputs thereof.

Referring back to norgates 1541 to 1543, which are energized by an input signal indicating a reading of $\bar{1} \bar{2} \bar{3} \bar{4} \bar{5} \bar{6}$, $\bar{1} \bar{2} \bar{3} \bar{4} \bar{5} \bar{6}$ and $\bar{1} \bar{2} \bar{3} \bar{4} \bar{5} \bar{6}$, respectively, the outputs of the norgates 1541 to 1543 are fed to a pair of norgates 1712, 1714 by means of conductors 1716, 1718, 1720. Thus, the output of gate 1541 is impressed on gate 1712, the output of gate 1542 is impressed on gate 1714 and the output of gate 1543 is impressed on both gates 1712, 1714. Also, the output of gate 1604 is fed by means of conductor 1721 to gates 1712, 1714, the output of gate 1606 to gate 1714 and the output of gate 1608 to gate 1712. The output of gate 1712 is fed to an inverter gate 1724, which inverts the signal and feeds it to a driver circuit 1726 in controlling relation with a fifth interposer means 1728. Similarly, gate 1714 is connected to a gate 1732 which inverts the binary zero input signal thereto and impresses the binary one signal in controlling relations on a driver circuit 1734 which in turn controls a sixth interposer means 1736. Each of the gates 1682 to 1688, 1724 and 1732 are controlled by an inhibit signal provided on a conductor 1740 connected to the typewriter function logic circuit to be described in conjunction with FIGURE 25. The signal level on conductor 1740 is normally at a binary zero level to enable gates 1682 to 1688, 1724 and 1732 except in the situation wherein the system is in the nonprint mode. In this mode,

5 a binary one level signal is impressed on conductor 1740 to inhibit the outputs of the gates 1682, to 1688, 1724 and 1732 and preclude the automatic actuation of the typewriter interposers. Thus, the signals are fed from the nonprint gates 1460 to 1474 and 1484 directly to the punch section and the typewriter unit is bypassed.

As is common in the art, the typewriter unit 75 is provided with a clutch mechanism 1744 which advances the information stored in the interposers 1632 to 1638, 1728, 1736 to the printing mechanisms of the machine. The signals feeding out from gates 1682 to 1688, 1724, 1732 are impressed on a seven input norgate circuit 1748 by means of a plurality of conductors 1750 to 1760. As each interposer is activated by a binary one output from gates 1682 to 1688, 1724, 1732, the binary one output signal is fed to the gate 1748, thereby providing a binary zero at the output terminal thereof. This latter binary zero signal is impressed on a gate 1764 which also has an input from inhibit conductor 1740. The binary one output from gate 1764 is fed to a driver unit 1768 by means of a conductor 1770.

25 Thus, as any one interposer is actuated, the machine clutch 1744 is also energized to translate the information stored in the interposers. In the situation where none of the interposers are actuated and the output terminals records a reading in any of the eight channels of the reader 77, the input norgate 1544, connected to $\bar{1}, \bar{2}, \bar{3}, \bar{4}, \bar{5}, \bar{6}$ and $\bar{7}, \bar{8}$ outputs from the reader logic section 1098, 30 will have a binary zero impressed on each of its input terminals. A binary one will be present at the output terminal of gate 1544, which will be impressed on gate module 1748 by means of a conductor 1774. Thus, if none of the interposers 1632 to 1638, 1728, 1736 are actuated, the signal from gate 1544 will actuate the clutch 35 1744 through gates 1748 and 1764.

In operation, and assuming that an output of binary zero is present at output terminals 1107, 1115, and 1116, a binary zero will appear at the inputs to gate 1503 and the inputs to all of the other gates of the group 1501 to 40 1544 will be at a binary one level. The output of gate 1503 will rise to a binary one level which is fed to gates 1570 and 1590. The rest of the gates will be at a binary zero output level which is fed to the inputs to gates 1572, to 1588, 1596, 1600. The binary zero output of gate 1570 45 is impressed on the input terminal at gate 1610 and this signal is inverted and impressed on gates 1650, 1652, 1654, 1656. The binary zero signal is fed to the input of gates 1682 to 1688 during the strobe time. Simultaneously, the output of gate 1503 is impressed on gate 1590 to produce a binary zero level signal at its output terminal. This signal is inverted by gate 1604 and the binary one level signal is impressed on gates 1712, 1714 50 by the conductor 1721, and a binary zero appears at the input to gates 1724, 1732 which inverts the signal to produce a binary one level signal at the drivers 1726, 1734 and interposers 1728, 1736 are activated.

55 Turning back to the binary one signal on the output conductor of gate 1503, this signal produces an output at gate 1610 which produces a binary one input level at gates 1650, 1652, 1654, 1656. The binary zero outputs of these latter gates are inverted by gates 1682 to 1688 to activate drivers 1692 to 1698 and thence interposers 1632 to 1638. Thus, all of the interposers 1632 to 1638, 1728, 1736 will be actuated at such time as a binary zero strobe signal appears on lead 1454 (FIGURE 22). Also the outputs of gates 1682 to 1688, 1724, 1732 are fed to 60 gate 1748 to produce a binary zero at the input to gate 1764. Thus during the strobe signal, the clutch 1744 will be pulsed through driver 1768 and the information received at inputs 1500 is passed to the interposers and to the typewriter 75. Thus, the gates just referred to are utilized to control a plurality of six interposers in the typewriter machine itself and the typewriter clutch solenoid.

Referring to FIGURE 24, there is illustrated a table 1780 of a representative code, chosen for illustrative purposes, illustrating a typical code which may be utilized in the system described above. The table has been broken up into two sections, that is, the upper shift and lower shift mode. As is seen from the table, the actuation of the first four interposers may represent eight characters depending on the combinations of five and six or lack thereof and whether the machine is in the upper shift or lower shift mode. Assuming the machine interposers one, two, three and four are actuated and the machine is in the upper shift mode, a capital "G" will be printed. Similarly, a "P" will print with the actuation of interposers one and three and an "h" when interposers one and six are actuated, the "P" being an upper shift mode and the "h" a lower shift. Each of the general characters normally found on a typewriting machine are illustrated at 1780 and by observing the column of interposers at the head of a column of characters and correlating the right side interposers, any particular character on a keyboard may be coded. Thus, the connections between the output terminals 1100 to 1119 and the input terminals may be made in accordance with a program which will produce an activation of the proper interposers 1632 to 1638, 1728 and 1736 at the typewriter 75 for a particular code punched in the tape being fed through the reader unit.

THE TYPEWRITER AND PUNCH FUNCTION LOGIC

Referring to FIGURE 25, there is illustrated a plurality of norgates 1784 to 1822 which consist of the remainder of the sixty-four input gates of the reader input logic including the group of gates 1501 to 1544. The gates 1784 to 1822 comprise means for providing an input circuit to operate certain machine functions within the typewriter unit 75. These signals are utilized to perform certain machine functions such as index, tab, upper shift, lower shift, carriage return, space, back space, print restore, nonprint, skip stop, tape skip, reader on, punch one on, punch off, punch two on and delete. It is to be understood that other machine functions in addition to those enumerated may be incorporated into the system in accordance with the desires of the user. As will be seen from the following description, the reader on portion has been so devised that a single reader signal will successively turn the main reader on, then the auxiliary reader, and back to the main reader, etc., with the same signal code. Thus, it is not necessary to provide separate signals to control the main reader and the auxiliary reader. The norgates 1784 to 1822 are interconnected with a machine function control circuit 1830 to control the operation of the operating mechanisms of the typewriter 75.

As was stated above, the norgates 1784 to 1822 are provided with inputs to a plurality of input hubs 1834 from the various bit sections, that is, the one, two and three bit section 1098a, four, five and six bit section 1098b and the seven and eight bit section 1098c, and these outputs are fed to the norgates 1784 to 1822 in accordance with a particular code corresponding to the code chosen for the particular machine functions enumerated above. The outputs of gates 1784 to 1822 are impressed on a plurality of output hubs 1836 which are in turn fed to a plurality of input hubs 1838 which correspond to the machine functions enumerated at the legend to the left of FIGURE 25. While it is to be understood that any system of interconnection may be used, a first gate to first input terminal connection, etc., will be described for purposes of simplicity. Referring to the tab function, it is seen that the output from norgate 1786 at terminal 1836 is fed to the tab input terminal 1840, and through a diode 1842, for a purpose herein-after explained in conjunction with the format control system, is fed by means of a conductor 1844 to flip flop 1848.

The signal is fed to the set side 1850 through an RC coupling circuit 1854 and through a resistor 1852 which is in shunt relation to the load. The resistor 1852 is utilized to provide a discharge path for the capacitor in the RC coupling circuit 1852. Flip-flop 1848 is at a normally reset condition wherein the set side 1850 is at a binary one and the reset side 1858 is at a binary zero. The signal from the input terminal, at a binary one when the tab code is received, will switch the flip flop 1848 to the opposite condition thereby putting a binary zero signal on the input to a norgate 1862. This signal is inverted to a binary one level and fed to an emitter follower circuit 1864 and through a driver circuit 1866 to the tab solenoid 1868 on the typewriter. The flip-flop 1848 and additional current amplifiers in the form of the emitter-follower 1864 and driver circuit 1866 are required due to the large coil contained in the tab solenoid 1868.

Normally, a binary zero signal is also fed to norgate 1862 by means of a conductor 2080 which provides a capability for inhibiting the norgate when a binary one level signal is put on the input terminal to norgate 1862, as will be hereinafter explained. The flip-flop 1848 is reset to its normal condition by means of a conductor 1876 from the reader control circuit which receives a signal from a tape advance reluctance pickup. The reset signal is impressed on the reset side 1858 through a norgate 1878 which inverts the binary zero signal to a binary one level, the signal being fed through a coupling circuit 1880 to the flip-flop 1848. Thus the flip-flop 1848 is reset to its normal condition to receive the next tab pulse. The signal from the tape advance reluctance pickup unit is provided when the tape starts to advance and thus is seen to generate a pulse every 65 seconds, corresponding to the cyclic rate of the reader.

Referring back to the input section, the output from the next norgate 1788 is fed to an input terminal 1884 corresponding to the upper shift function and, through a diode 1886 and conductor 1888, is fed to a coupling circuit 1890 which passes the signal to the set side 1892 of a flip-flop 1894. As in the above case, a large resistance 1896 to ground has been provided in order to shunt the discharge current of the RC circuit. With the incoming binary one signal, the flip-flop 1894 will be switched to the binary zero state at the output terminal of the set side 1892, which is then fed to a norgate 1898. The signal is inverted by the gate 1898 and the binary one signal is fed to emitter-follower 1902 and thence to driver circuit 1904. The output of the driver 1904 is fed to the coil of an upper shift mechanism 1906 to provide the upper shift function for the typewriter 75. The upper shift mechanism 1906 is magnetically coupled to a shift pickup coil which is connected into the reader control circuit, illustrated in FIG. 26, and when the machine completes its upper shift cycle, the shift pickup coil generates a signal which is fed by means of a conductor 1908 to an RC circuit 1910. The coupling circuit 1910 generates a spike on the positive going edge of the pulse from the shift pickup coil and feeds the output thereof to the reset side 1912 of the flip flop 1894 thereby resetting the flip-flop unit. It is to be noted that the shift pickup coil feeds the output signal to a pair of resistors which are grounded at their interconnections and the upper resistor provides the resetting signal for flip-flop 1894. This function will be more fully explained in conjunction with the explanation of the reader control circuit.

A lower shift input terminal 1920 is correspondingly connected to the output 1836 of the norgate 1790 and fed by means of diode 1922 and a conductor 1924 to another flip-flop circuit 1930 through a coupling circuit 1932. Again a grounding resistor 1934 has been provided and the signal switches the set side 1935 of the flip-flop 1930 from the binary one state at its output to the binary zero state, which is in turn fed to a norgate 1938. The output of gate 1938 is fed through a driver circuit 1940 to a lower shaft solenoid 1942 and, as was the case

in conjunction with the upper shift feature, the shift pickup coil feeds a signal to the reset side 1948 of the flip-flop 1930 through a conductor 1950 and an RC coupling circuit 1952. Thus the flip-flop 1930 is reset on the completion of the lower shift operation.

Each of the flip-flops 1848, 1894, 1930 described above are initially set to a binary zero by means of an NPN transistor 1960 (FIGURE 26) connected thereto by a conductor 1962. The reset sides 1858, 1912, 1948 of the flip-flops are connected in the collector 1964-emitter 1966 circuit of transistor 1960 and, by feeding a signal to a base electrode 1968, the transistor 1960 is caused to conduct. With the conduction of transistor 1960, the reset sides of each of the flip-flops 1848, 1894, 1930 are grounded through a plurality of diodes 1974, 1976, 1978 thereby setting the initial conditions of the flip-flops connected to the tab, upper shift and lower shift function solenoids. This initial setting function is performed only on the initial power turn-on and the resetting function is performed thereafter as described above. As in the situation with all of the transistors of the system, a turnoff biasing resistor 1980 is connected to a negative 5 volts. The base signal is derived from an initial turn on circuit which sets all of the flip-flop units described when power for the system is initially turned on.

Referring now to the carriage return function, the gate 1792 is connected to the carriage return input terminal 1986. The input signal is fed to a gate 1987 through a diode 1988 and conductor 1990, wherein the signal is inverted from a binary one to a binary zero. The binary zero signal is fed to a gate 1994 which inverts the signal to a binary one and then feeds the binary one to a driver circuit 1996 and directly to carriage return solenoid mechanism 2000. It is to be noted that the gate 1994 is provided both for the inhibit feature which is provided by means of the conductor 2080 and signal from the same section as provided the signal to inhibit the functions of the tab, upper shift and lower shift, and to provide a sufficient current signal for the carriage return solenoid. The index, space and back space features are provided by similar circuitry wherein the output signals of the plurality of norgates 1784, 1794, 1796 are impressed on input terminals 2004, 2006, 2008. These latter signals are fed to a set of norgates 2010, 2012, 2014 to provide a suitable driving signal for the index, space and back space solenoid mechanisms 2018, 2020, 2022, respectively. As in the above situation, the inhibit function is provided by the norgate 2026, 2028, 2030 and the current to the coils is boosted by a plurality of driver circuits 2034, 2036, 2038, respectively.

The print restore and nonprint functions are provided by feeding the output of gates 1798 and 1800 to the print restore and nonprint input hubs 2050 and 2052, respectively. Referring first to the nonprint mode, the nonprint signal is fed from the input terminal 2052 to the set side 2054 of a flip-flop unit 2056 through a diode 2060 and a conductor 2062. The flip-flop unit 2056 is normally at a binary zero level at its output terminal on the reset side 2066 and a binary one at the output terminal of its set side 2054. The set and reset designation for flip-flop 2056 is utilized for sides 2054 and 2066, respectively, due to the fact that the initial conditions are provided by impressing a signal on the reset side 2066. This designation will be utilized in situations where main signals are fed to both sides of the flip-flop, as in the case of flip-flop 2056. The binary one input signal is inverted by a gate 2070 and the trailing edge of the pulse is fed through a positive coupling circuit 2072 to switch the state of flip-flop unit 2056 thereby placing a binary one at the output terminal of the reset side 2066 and a binary zero level at the output terminal of the set side 2054. The binary one pulse is fed through an emitter follower 2078 to an inhibit conductor 2080, which is connected to each of the norgates 2026, 1862, 1898, 1938, 1994, 2028 and 2030, thus totally inhibiting

any of the machine function signals which may be fed to these latter gates. The binary one output signal from the reset side 2066 is also fed by means of a conductor 2084 and conductor 2086 to the interposer output gates through an emitter follower 2088.

The binary one output level at the set side 2054 of the flip-flop unit 2056 places a binary one inhibit signal on conductor 2094 which is impressed on the input to a norgate found in the select/all circuit, to be hereinafter explained in conjunction with FIGURE 38. Also, the binary one output at the set side 2054 is fed to a gate 2096 by means of a conductor 2098, the gate 2096 having a second input from a flip-flop 2100 which has its reset side 2102 at a normal binary zero output level thereby putting a binary zero at the input to gate 2096 through emitter follower 2106 and conductor 2108. When the condition of flip flop unit 2056 is switched, thereby putting a binary zero at its set side 2054, the gate 2096 is caused to produce a binary one at its output terminal 2112 and this output is placed at the input terminal of a second gate 2114. This binary one is inverted by gate 2114 and fed to an emitter follower 2116 which produces a binary zero at the output conductor 1488 which is connected to the inhibit circuit in the nonprint gate 1460 to 1474 and 1484 in FIGURE 22.

Thus the inhibit is removed from these nonprint gates to retain the normal control functions provided by the outputs of these gates. It will be noted that all of the inhibit signals being provided to the machine function and machine character circuits still allow the machine to read the normal codes provided therein by the tape. While the system is in the nonprint mode, the tape will skip through the reader and read each code therein but will not print the information on the typewriter unit 75 but will punch a tape identical to that in the reader in the punch unit 81. In accordance with this description it will be seen that the machine is capable of reading the print restore code which is impressed on terminal 2050 by means of output gate 1798. The signal from the print restore terminal 2050 is fed through a conductor 2120 to a norgate 2122 and thence through a coupling circuit 2124 to the reset side 2066 of the gate 2056. Thus the flip-flop unit 2056 is restored to its normal state, that is, with a binary zero at its reset side output terminal and a binary one signal at its set side and the logic circuit will be restored to its normal situation whereby the inhibits are removed from the machine function output gates and the character output gates.

The flip-flop unit 2056 is initially set by the operation of a signal placed on conductor 1962 which was utilized to set the initial conditions of flip-flops 1848, 1894 and 1930. This signal is also fed through a diode 2130 and the conductor 2084 to initially ground the reset side 2066 of flip-flop 2056. The binary one signal on conductor 2086 is also fed to a plurality of grounding circuits 2134 through an emitter follower 2136 and a conductor 2138. A plurality of output hubs 2140 are connected to inhibit certain functions in the nonprint mode in auxiliary equipment being utilized with the system. For example, certain signals may be fed from the system to a computer, information processing units or the like wherein it is desired to stop the flow of these signals to the input thereof. Accordingly, the output hubs 2140 may be connected to the input hubs of the auxiliary equipment to ground the signals at such time as the system is in the nonprint mode.

Thus, with the foregoing circuit, the machine function and character gates are all inhibited in that their outputs will not be passed through to the respective machine function solenoids or interposer solenoids. However, the system is still capable of reading the tape as the tape is being passed through the machine at as rapid a rate as possible. In order to provide a continuous operation of the reader control circuit, as will be hereinafter explained, the binary one signal on conductor 2080 is fed through

a diode 2144 and a conductor 2146 to the reader control circuit illustrated in FIGURE 26 by means of an output conductor 2150. The operation of this signal will be more completely described when a description of the reader control circuit is provided.

Referring now to the skip-stop and tape skip functions, the output of gates 1802 and 1804 are fed to a skip-stop input terminal 2154 and a tape-skip terminal 2156, respectively. The binary one tape-skip input signal is fed through a conductor 2158 and a diode 2160 to the set side 2164 of the flip-flop unit 2100 by means of an RC coupling circuit 2166. As was stated above, the flip-flop 2100 is normally at a binary zero output level at the output terminal of its reset side 2102 and a binary one level at the output terminal of its set side 2164. The input signal switches the condition of the flip-flop unit 2100 whereby a binary one appears at its reset side output terminal and a binary zero appears at its set side 2164. The pulsing of the flip-flop unit 2100 provides the binary one output signal from the reset side 2102 through the emitter follower unit 2106 and conductor 2108 to a coupling circuit 2170. The output of coupling circuit 2170 is fed to the side 2054 of the nonprint flip-flop unit 2056 to change the state of the flip-flop 2056 whereby a binary one appears at its true side 2066 output terminal and a binary zero appears at the not true side 2054. Thus the identical circuitry described above in conjunction with the nonprint mode is utilized with the exception of the signal to the nonprint gates 1460 to 1474 and 1484, the signal being provided on conductor 1488. It will be seen that the binary one signal fed to coupling circuit 2170 is also fed to the lower input terminal of gate 2096 thereby putting a binary one on its input terminal. The output at this gate 2096 will be at a binary zero level, this binary zero being inverted by gate 2114.

Thus, a binary one inhibit signal is placed on the nonprint gates described in conjunction with FIGURE 22 through emitter follower 2116 and conductor 1488. In the tape skip mode, the binary one signal at the reset side 2102 is fed through a conductor 2176 to a plurality of grounding circuits 2180, 2182, 2184 and 2186 to ground the terminals corresponding to the punch and reader on-off switches, as will be hereinafter explained in conjunction with the reader and punch unit on-off feature. This signal is fed through an emitter follower 2188 to provide the necessary current level to drive the four grounding circuits 2180 to 2186 described. The binary one signal from the reset side 2102 of flip-flop 2100 is also fed through the emitter follower 2106 and a diode 2192 to a conductor 2194 which is connected to the output conductor 2150 connected to a grounding circuit in the reader control circuit through conductor 2146. Thus the control function described above in conjunction with the output from the reset side of flip-flop 2056 and impressed on conductor 2150 is present in the tape skip mode. In this way the reader unit will skip tape through the machine and will not punch tape while still maintaining the operation of the reader control circuit, as will be more fully described hereinafter.

When it is desired to remove the machine from the tape skip operation, a signal is fed from the gate 1802 to the skip stop terminal 2154. This signal is impressed on the reset side of flip flop 2100 by means of a conductor 2196 and an RC circuit 2198 thereby resetting the flip flop 2100 and removing the binary one signal at the output terminal of the reset side 2102. Accordingly, the set side 2066 of flip-flop 2056 is grounded through RC coupling circuit 2199 and conductor 2201 returning the flip-flop 2056 to its normal state. Thus the inhibits are taken off the machine function norgates and the character norgates as was the case with the print restore signal described above.

The lower portion of the machine functions logic circuit 1830 is provided with a delete code norgate 4252 which is illustrated as having a plurality of ten inputs but

may be designed to have a greater or lesser number of inputs. The gate 4252 includes a plurality of input terminals 4254 which receive code signals from the output terminals 1100 to 1119 in the reader input logic section. The codes which are selected to be patched into the delete gate 4252 are those codes which may be punched into the tape passed through the reader but which the user does not want to print or punch. However, it is necessary that the reader control circuit receive a pulse indicating the reading of these delete codes to provide a running pulse for the control loop 2414. Thus the output of gate 4252 is fed to the flip-flop 2454 (FIG. 26) by means of a conductor 4258 and the conductor 2204. Accordingly, the signal at the output terminal of gate 4252 serves the same function of continuing the operation of the control loop 2414, as did the output pulse from gate 2200, while eliminating the coded signal from the typewriter and punch units. Also, a stop code terminal 4260 is included in the input hubs which is connected to the reset side 2399 of flip-flop 2400 by means of a conductor 4264 and an RC coupling 4266. The stop code signal provides an automatic stop feature in the system which is generally identical to the stop function provided by the manually actuated stop switch 2506.

Each of the signals received on terminals 2050, 2052, 2154 and 2156 are impressed on a norgate module 2200, having an output at output conductor 2202 which is in turn impressed on conductor 2204. This conductor is connected to the reader control circuit to provide a pulse each time one of the enumerated functions has been read by its respective flip-flop units or, on the other hand, received at its input terminals such as at the print restore-non-print, skip-stop and tape skip input terminals. With the signal on conductor 2204, the reader control section 35 is signalled that an input signal has been received and the reader control circuit is cycled to provide the necessary control functions as will be hereinafter explained. Also, when the flip-flop 2100 is pulsed in the tape skip mode, the binary one signal from emitter follower 2106 is fed to a conductor 2210 and a grounding circuit 2212 to ground the input from the print restore input terminal 2050.

In this manner, only a skip-stop signal will restore the system to its normal operation and a print restore signal will be immediately grounded by grounding circuit 2212 to make it ineffectual to restore the system to its normal operation. The tape skip flip-flop 2100 is initially set by means of a conductor 2220 which is connected to the juncture between the emitter follower 2384 and coupling circuit 2388 in FIGURE 26. The binary one signal from the gate 2370 is fed through an RC coupling circuit 2222 to the reset side 2102 of flip-flop unit 2100 initially setting the flip-flop on power turn on as with the other flip flops described in conjunction with the setting circuit. A setting signal is also provided to flip-flop 2100 by means of a conductor 2228 and RC circuit 2230 from the reader control circuit, as will be hereinafter explained. This setting signal is also fed to flip-flop 2056 through a conductor 2232 and RC coupling 2234.

A manual operation has been provided for the nonprint and the tape skip function wherein a nonprint switch 2269 has been provided on the manual keyboard of the typewriter unit 75. The nonprint switch generally comprises a switch armature 2262 which is connected at one end thereof to a +15-volt power supply through a conductor 2264 and the other end being in engagement with a normally closed terminal 2266. The switch is adapted to be moved to a normally open terminal 2270 which is connected to a resistor 2272 at one end thereof, the other end being connected to ground. Thus, when the switch is moved to the normally open terminal 2270, the current from the +15-volt power supply is conducted through conductor 2264, armature 2262 and resistor 2272. The positive voltage at the point 2274 is fed through

an RC coupling circuit 2276 and conductor 2278 to the set side 2054 of flip-flop 2056. Thus the binary one signal is fed to the flip-flop unit 2056 to switch the conditions of the flip-flop unit thereby putting a binary one on its reset side 2066 output terminal and a binary zero on its set side 2054 output terminal. In this condition the circuit will operate in a manner identical to that described above wherein a signal was received at the nonprint input terminal 2052. A signal is also provided to the reader control circuit by means of a diode 2280 and a conductor 2282. With this signal the reader control circuit is maintained in operation to continuously provide the control functions necessary to the operation of the reader.

A manually operated tape skip function is also provided wherein a tape skip switch 2290 is provided on the keyboard of the typewriter unit 75 and is adapted to be manually actuated to skip tape through the reader unit 77 without printing on the typewriter machine 75 or punching a tape in the tape punch unit 81. The tape skip switch generally comprises a movable switch arm 2292 which is adapted to be moved between a normally closed terminal 2294 and a normally open terminal 2296. The switch arm is connected through the conductor 2264 to the +15-volt power supply and when the switch 2290 is actuated to the normally open terminal 2296, the +15-volt power supplies current through a diode 2298 and a resistor 2300. The voltage drop across the resistor is fed to the set side 2164 of flip-flop unit 2100 by means of a conductor 2304 and a coupling circuit 2166. In this manner the flip-flop unit 2100 is switched to its tape skip condition as in the above described automatic tape skip situation. The normally open terminal 2296 is also connected to conductor 2282 through a diode 2308 to provide the necessary signal to the reader control circuit, as was described in conjunction with the nonprint manual switch 2260.

THE READER CONTROL CIRCUIT

As was stated above, at a certain point in the cyclical operation of the reader system, it is necessary to strobe all of the reader logic circuits, that is, the norgates, to provide a synchronous operation of the reader logic. Accordingly, a reader logic strobe signal has been provided which will inhibit the reader logic until such time as the strobe signal reduces the inhibit signal to zero thereby allowing the information stored in the reader logic to be passed forward through its preprogrammed sequence. Also, certain of the machine functions require a longer time to complete the operation than the 65-millisecond cyclic time of the reader unit. Accordingly, it is necessary to delay the reader operation to allow sufficient time to complete these operations and certain circuit means have been provided to control the operation of the reader control circuit in accordance with the actual completion of these latter operations.

Also, it is necessary that the reader clutch be provided with a signal to advance the clutch one position each time a bit character has been read through the reader section. Accordingly, a clutch advance signal is generated in the reader control circuit to actuate the reader clutch in accordance with the cyclic time of the typewriter unit or in accordance with the completion of operation cycle in the case of operations requiring longer than the basic machine cycle. More specifically, at the end of each of the character, numeric or function signals, a signal must be provided which indicates the completion of either the character, numeral or function signal to allow the tape reader to advance to the next position on the tape. This is necessary because certain of the functions take longer than others; for example, the carriage return may take longer to complete than the normal reading and printing of a character or numeral. Thus a provision must be made to keep the system in sequence or in synchronism with the operation of the typewriter unit and the functions being performed. All of these features, plus certain others which

will become apparent, are provided in a reader control circuit 2350 which will now be described with reference to FIGURE 26.

The initial conditions in the reader control circuit 2350 and the flip flop units in the reader and typewriter logic sections are set by turning on the main power to the system to actuate a condition set circuit 2352 generally comprising a capacitor 2354 connected between a +15 volts at a terminal 2356 and ground through a relatively large resistor 2358. Thus as the power is turned on and the 15-volt source rises to operating voltage, a pulse is fed to a norgate 2364 by means of a conductor 2366, the gate 2364 inverting the pulse and feeding it to norgate 2370 through a conductor 2372. A resistor 2374 to ground is provided between the 15-volt power supply and the capacitor by means of a conductor 2376 which provides a discharge path for the capacitor 2354. Also, a blocking diode 2378 is provided in the circuit of norgate 2364 to protect the base-emitter circuit of the transistor contained therein from the negative 15-volt discharge on the capacitor 2354 when the power is turned off. The binary one signal at the output of gate 2370 is fed first through an emitter follower 2384 to a single shot multivibrator 2386 by means of a negative pulse coupling RC circuit 2388 which then provides a positive output at an output conductor 2390 of the single shot multivibrator 2386.

The leading edge of the output of the single shot multivibrator 2386 is fed to a ground circuit in the punch control circuit, and the pulse is also fed through a norgate 2392 to another ground circuit in the punch control circuit, thereby providing a trailing edge to set the initial conditions of the flip-flops in the punch control circuit, as will be hereinafter explained. The positive output pulse from norgate 2370 is also fed through a conductor 2396 and another conductor 2398 to the reset side 2399 of a flip-flop circuit 2400 by means of a positive capacitive coupling circuit 2402 to provide a setting signal for the flip-flop 2400. The positive signal from gate 2370 also provides the signal pulse for transistor 1960 to initially ground the flip-flop units of the typewriter function logic circuits through a conductor 1962. The signal pulse is fed to transistor 1960 through an emitter follower 2408 and resistor 2410 to the base electrode 1968 thereby controlling the conducting or nonconducting state of the transistor 1960.

In describing the reader control circuit, it will be best for a complete understanding of the control functions performed by the control circuit that a description of a control loop 2414 contained therein be described and the ancillary control signals, starting signals and output signals be related to the control loop 2414. For simplicity, a node 2416 will be considered as the starting point for the loop 2414 in that certain control signals are fed into the node 2416 as will be seen as the description proceeds. Also, a further description of the starting flip-flop 2400 will be held in abeyance in favor of a complete description of the control loop 2414. It is to be understood that loop 2414 operates in synchronism with the operation of the reader and typewriter units to cycle each time the reader clutch or print shaft turns or an end of function operation signal is received.

Assuming a positive pulse is generated and passed to the node 2416, the pulse impressed at the node is fed to the single shot multivibrator 2420 by means of a conductor 2422. The positive going output pulse from multivibrator 2420 is fed to the negative capacitive coupling circuit 2424 by means of a conductor 2426 wherein the trailing edge of the pulse is outputted from the coupling circuit 2424. The output of the coupling circuit 2424 is fed to a second single shot multivibrator 2428 by means of a conductor 2430 and the positive going output pulse is in turn fed to inverter norgate 2434 thereby inverting the pulse. This inverted pulse is fed to the reader logic strobe and reset section described in conjunction with

FIGURES 20, 21 and 22 by means of the conductor 1454, the strobe and reset pulse decreasing from a binary one level to a binary zero volt level. The signal is fed through the emitter followers 1450, 1458 and thus to the respective gates 1140 to 1154, 1290 to 1304, 1404, 1406, 1410 and 1412 to strobe any information contained in these norgates. Similarly, the pulse is also fed to the gates 1460 to 1474 and 1484 by means of the conductor 1492 through emitter follower 1490. The pulse is also fed through an emitter follower 2440 by means of a conductor 2442 and coupling circuit 2444 to each of the flip-flop circuits 1120 to 1143 to reset each of the flip-flops at the trailing edge of the pulse and prepare them for the next bits of information to be fed from the reader input. It is to be noted that the pulse strobes each of the norgates to output the information stored in the reader flip-flops and the trailing edge resets all of these flip-flops.

Referring back to FIGURE 26, the binary zero pulse is then fed from norgate 2434 to a norgate 2450 which inverts the pulse to a binary one level and feeds the pulse to the reset side 2452 of flip-flop circuit 2454 by means of a coupling circuit 2456 and a conductor 2458. The pulse to flip-flop unit 2454 switches the reset side 2452 to the binary zero level at its output and the set side 2462 to a binary one output level thereby giving a binary one output at conductor 2464. The signal on conductor 2464 is impressed on a norgate 2463, to produce a binary zero at the output thereof in the event a binary zero level signal is present on conductor 2457. The input to conductor 2457 is provided from any desired interlock circuit, which may take the form of an interlock signal from a computer, etc., whereby an inhibit signal for the loop 2414 is generated. The output from gate 2463 is impressed on an inverter gate 2463, which inverts the binary zero output of gate 2463 to a binary one level. This latter binary one signal is fed through an input conductor 2468 to a norgate 2470 which tends to inhibit the norgate 2470 until such time as the state of flip-flop 2454 is changed by a binary one pulse to its set side 2462. The output pulse from single shot multivibrator 2420 is also fed through the conductor 2426 to a norgate 2474 which inverts the incoming pulse and feeds it to norgates 2476, 2478 by means of an emitter follower 2480, thus putting a zero signal into norgate 2476, 2478. Certain of the inputs to gate 2476, 2478 are provided from a reader switching flip-flop illustrated in FIGURE 25.

Referring back to FIGURE 25, readers one and two are controlled by means of an output signal from gate 1806 being fed to a diode steering network flip-flop 2490. The output of the flip-flop 2490 is impressed on the input to gate 2476 by means of a conductor 2492 to turn reader one on and a second output is impressed on gate 2478 by means of conductor 2494 to turn reader two on. As described in conjunction with FIGURE 16, each pulse into the diode steering network flip-flop 2490 changes the state of the flip-flop to alternately place binary one outputs on conductors 2492, 2494. Thus, an inhibit signal is placed into one of the gates 2476, 2478 to inhibit the output thereof and control which reader is being utilized. The condition of a signal being received at input terminal 2554 is incorporated into gate 2200 as in the situation of the nonprint, tape skip, etc., modes by means of a conductor 2495 to provide an output on conductor 2204, for a like purpose. Gate 2476 includes an output terminal 2496 which is connected to the clutch mechanism of reader one to provide an actuating pulse to the reader and operate the clutch in successive increments. Similarly, an output terminal 2498 is provided from gate 2478 to similarly actuate the clutch mechanism of reader two. A pair of input terminals are additionally provided for each gate 2476, 2478 which will have binary zero level signals thereon at such time as the readers are to be actuated as will be hereinafter explained.

The start-stop flip-flop 2400 has been provided with and is connected to a pair of start-stop switches 2504,

2506, respectively, which are utilized to set flip-flop 2400 in one condition or the other. The start switch 2504 generally comprises a switching arm 2510 which is connected to a capacitor 2512 through a conductor 2514 at one side thereof and the other side of the capacitor 2512 is connected to ground. The switching arm engages a normally closed terminal 2518 and is adapted to be operated to a normally open terminal 2520 connected through a conductor 2522 and a resistor 2524 to a +15-volt power supply. Thus, as the switch 2504 is operated to the normally open position 2520, the capacitor 2512 is charged to approximately +15 volts and, when the switch 2504 is released to its normally closed position 2518, the capacitor discharges through a diode 2528 to a norgate 2530, which then inverts the position pulse to a binary zero level pulse. The binary zero level pulse output is fed to a norgate 2534 and thence to a positive coupling circuit 2536 through a conductor 2538, thereby feeding a spike pulse to the set side of flip-flop 2400.

The switching of flip-flop 2400 provides a binary zero output at the set side 2542 thereof and this zero output is fed first to the norgate 2470 through a conductor 2544 and an emitter follower circuit 2546 and also to the norgates 2476, 2478 through conductor 2550 thereby putting a binary zero on the input conductors of gates 2450, 2470, 2476, 2478. The fourth input terminal to each of gates 2476, 2478 is normally at a binary zero level, except when a malfunction is sensed by the parity check circuit, thereby placing all binary one inputs to norgate 2476 in the case of the use of reader one and to gate 2478 in the case of reader two. With these conditions present and no parity error, binary one pulse is fed to the clutch of, for example reader one, thus advancing the reader clutch. As is seen from the above described circuitry, if the diode steering network flip-flop 2490 were pulsed again to turn reader one off and turn reader two on and putting a binary zero on the upper side of flip-flop 2490, then reader two would be turned on. The pulsing signal for the reader unit is fed from, for example, gate 1798 to an input terminal 2554 and conductor 2556 (FIGURE 25). As was explained above, only one gate need be utilized to provide the input signal for both reader one and reader two due to the use of the diode steering network in flip-flop 2490 and a single code designation.

As was stated above, a binary zero is placed on the input lead to norgate 2470 by conductor 2544. Also, a zero input is impressed on the upper input conductor 2560 from a pair of reluctance pickup units 2562, 2564 which are actuated at such time as the tape advance mechanism of either reader one or reader two is actuated. A binary one level signal is normally on the upper and middle input terminals to norgate 2470 due to the condition of conductor 2560 prior to a signal from the tape advance unit and to the output of the set side 2462 of flip-flop 2454 thereby giving a zero output at the output of norgate 2470. In the operation of the control circuit 2350, the reader shaft is provided with a clutch signal from gate 2476 or gate 2478, and when the reader shaft advances a reluctance pickup unit 2562 or 2564 sensing the advance of the tape at the end of the reader cycle and provides an output pulse. This output pulse is inverted through either of a pair of norgates 2568 or 2570, and an inverted signal of binary zero is fed to the set side 2563 of a flip-flop unit 2565 through an RC coupling circuit 2567. The flip-flop unit 2566 is provided to store the tape advance signal for a reason to be hereinafter explained.

During a portion of the period in which the signal on conductor 2560 is at a binary one level, the signal from a print shaft mechanism 2574 is at a binary zero level until the reluctance pickup unit generates a signal in advance of the signal from the tape advance pickup units 2562, 2564. This print shaft signal is inverted by a gate 2576 and inverted again by a second gate 2578 causing a binary one output pulse to be impressed on the set side 2462 of flip-flop 2454 by a coupling circuit 2582

and a conductor 2584. The coupling circuit 2582 takes the leading edge of the pulse and transforms it into a spike which is fed to the flip-flop 2454, thereby changing the condition of the flip-flop 2454 to a binary zero output at the set side 2462. This binary zero output is fed into norgate 2470 prior to the receipt of a signal from the tape advance reluctance pickup unit 2568, 2570. Thus, with the binary zero signals at each of the two input terminals corresponding to the conductors 2468, 2544, the zero level pulse from conductor 2560 is passed through gate 2470 and a positive pulse is obtained at the output of norgate 2470. This positive pulse is fed to the node 2416 through a diode 2587 and a positive pulse coupling circuit 2588 and the cycle in the loop 2414 is repeated. A resistor 2589 is provided to discharge the capacitor in the coupling circuit 2588.

Thus it is seen that each time the tape advances and the print shaft advances, thereby giving pulses at norgate 2470, the cycle about the loop 2414 will be maintained and a continuous stream of strobing and reset pulses will be transmitted on the strobe and reset conductor 1454 to reset the reader input flip-flops and also strobe the reader output logic norgates.

To initially start the cycle of the cycling of the loop, the start button is first moved to the normally open position 2520 to charge the capacitor 2512 and then allowed to move to the normally closed position 2518 and the capacitor 2512 discharges through the diode 2528. The positive pulse is fed to norgate 2530 which inverts, amplifies and squares the start spike from capacitor 2512 and the inverted pulse is fed to gate 2534. Gate 2534 inverts the pulse and in turn feeds it through the resistor-capacitor circuit 2536 to flip-flop 2400. This pulse switches the flip-flop 2400 to the opposite state giving a binary zero output on the set side 2542 and a binary one output on the reset side 2399. The reset side 2399 is connected through a coupling circuit 2604 and a conductor 2606 to the node 2416 which then passes the pulse to single shot multivibrator 2420 thereby starting the cycling of the loop 2414. The reset side 2399 is also connected to the input to gate 2450 through a gate 2607, which prepares the gate 2450 for the resetting signal from gate 2434. When it is decided to stop the control circuit, the stop button 2506 is placed in contact with a normally open terminal 2610 thereby putting a +15-volt pulse through a coupling circuit 2612 by means of a conductor 2614 to the reset side 2399 of flip-flop 2400. Thus, a binary zero is placed on the reset side 2399 output and a binary one on the set side 2542 output. This binary one from the set side 2542 is fed to norgate 2470 which inhibits the operation of the norgate thereby precluding any signals from the tape advance and print shaft from passing through.

However, there are certain functions which do not provide a tape advance signal and a print shaft signal. In these situations certain completion signals must be substituted for the tape advance and the print shaft signals in order to maintain the continuous operation of the loop 2414, thus providing an actuating signal for the reader clutch where desired, and also to provide a strobe signal for the reader logic section. Such situations are in the upper shift and lower shift, spacing, indexing, back spacing and carriage return. Accordingly, certain pickup signals are provided at the completion of each of these functions. Considering first the functions of upper shift and lower shift, a shift pickup coil 2650 provides a signal or a positive spike each time the machine comes out of the upper shift or lower shift operation. The coil 2650 is connected at its ends to a resistor 2652, representatively illustrated as a center tapped resistor, by means of a pair of conductors 2654, 2656. The center tap of the resistor 2652 is grounded by means of a conductor 2658. Each time the typewriter mechanism is actuated to the upper shift mode, current is generated in the coil 2650 in a first direction through the coil 2650 and resistor 2652 to pro-

duce a positive voltage at the node 2660 and the opposite is true when the machine goes in to lower shift wherein a positive voltage is generated at node 2662.

The upper shift signal is fed from the node 2660 to a gate 2668 which inverts the signal to a binary zero level and feeds this signal to the flip-flop unit 1894 described above. The signal is additionally fed to a norgate 2672, which then inverts the pulse to a binary one level pulse. This binary one signal is fed to a seven input norgate 2674 by means of an input conductor 2676 to produce a binary zero output pulse at the output terminal of gate 2674. This binary zero pulse is fed through a conductor 2680 and a coupling circuit 2682 to the set side 2681 of a flip-flop 2683. The flip-flop stores the signal and impresses it on a gate 2685, and thence through a diode 2687 and conductor 2689 to input of RC coupling circuit 2588. Thus, a pulsing signal is provided for single shot multivibrator 2420 through node 2416, which then restarts the cycle around the loop 2414 again. A similar occurrence is provided for the lower shift signal generated at the node 2662 wherein this signal is fed to gate 2674 through a pair of series gates 2688, 2890. The output of gate 2674 is impressed on node 2416 through coupling circuit 2682. The reset signal for flip-flops 2565, 2683 is provided through the conductor 2458 and a plurality of RC coupling circuits 2691, 2693.

The upper portion of the norgate 2674 has a third input conductor 2694 which is connected to gate 2696 which is connected to a single shot multivibrator 3028 and gate 3030 sensing the tab motion of the machine and feeding this input to the punch and reader section of the system or, more specifically to the typewriter input logic circuitry, to be hereinafter explained. The tab function is sensed and a binary zero signal is impressed on conductor 2694 when the pulse is received from the tab single shot multivibrator and this signal is inverted by means of an inverter gate 2696 to produce a binary one level output signal. The tab mechanism is actuated by operating the tab key or actuating the rotary solenoid to be described in conjunction with the typewriter input logic circuit. The binary zero input is fed to the input conductor 2694 of gate 2696 and the upper input conductor of gate 2674 to produce a pulse at the node 2416 through the circuit including an RC coupling circuit 2697, flip-flop 2683, gate 2685 and RC coupling circuit 2588.

Similarly, the space function is sensed in the typewriter input logic section by a reluctance pickup and the binary zero signal is fed to an input conductor 2698, the signal being fed to a gate 6072 (FIGURE 45) and the binary one signal from the output of the gate 6072 is fed to the upper input terminal of the lower section of gate 2674 by means of conductor 2698. The operation of gate 6072 will be explained in full when the description of FIGURE 45 as presented. Thus the output of the gate 2674 is dropped to a binary zero level to produce a pulse at the node 2416 through the circuit including flip-flop 2683. The back space function is similarly sensed as that of the space function and the signal is fed to gate 2674 by means of a conductor 2704 and the gate 2706. The output of gate 2706 is fed to the lower portion of gate 2674 by means of a conductor 2708.

The index function is sensed by a magnetic reluctance pickup unit 2712 which provides a positive spike to a pair of norgates 2714, 2715 which then impresses the output signal on an input terminal 2720 to gate 2674. The output of gate 2674 is dropped to a binary zero level which impresses a pulse on node 2416, as described above. The carriage return feeds an end of function signal from the reluctance pickup unit 2724 to an input conductor 2726 by means of a pair of gates 2728, 2730. Thus each time the machine performs a function, an end of function signal is generated in one form or another and fed to gate 2674 to provide a pulse to cycle the loop 2414. In this way the reader clutch is advanced and a strobing signal is provided to read the next bits of information

being passed through the system. Certain other input signals from the format control systems are fed to the index and carriage return input conductors to gate 2674, which will be explained in conjunction with the explanation of the FCS system.

Referring back to FIGURE 25 and to the situation wherein the machine is in the nonprint mode, that is, when a signal signifying nonprint has been received at the nonprint input terminal or the nonprint button has been actuated, the flip-flop 2056 is switched through norgate 2070 whereby a binary one signal is fed from the reset side of flip-flop 2056 to the emitter follower 2078, then to diode 2144 to conductor 2146, 2150. This binary one is, in turn fed to a grounding circuit 2740 (FIGURE 26) which provides a continuous ground to the point 2464 adjacent flip-flop 2454 by means of a conductor 2742. With a constant ground on the output of the set side 2462 of flip-flop 2454, a constant binary zero will be fed to the center input terminal to norgate 2470, and with the constant zero on conductor 2544, the reader control circuit 2350 will continue to cycle. This cycling will be continuous and producing strobe and reset signals until the print restore or skip stop signal, in the case of the tape skip mode, is received.

Thus were the print shaft on the reader is not being utilized in the nonprint operation, and flip-flop 2454 is not being cocked by a signal therefrom, a constant binary zero signal is being fed to the center input of norgate 2470, thus allowing the tape advance signal to pass through the norgate and on to the node 2416 through the coupling circuit 2588. When a print restore signal is fed to the print restore input terminal 2118, the signal is fed through norgate 2122 to reset flip-flop 2056 thereby taking the binary one signal from the output of emitter follower 2078. In this way the grounding circuit 2740 is disabled and the loop 2114 will operate in a manner similar to that described above wherein a signal is received from the print shaft.

In certain situations, the print shaft is not utilized and no function completion signal is received due to the fact that a typewriter function is not being performed. In order to provide the necessary control functions from the reader control circuit 2350, the gate 2200 (FIGURE 25) has been provided to sense the incoming signals for print restore, nonprint, skip stop, tape skip, reader on, punch #1 on, punch off and punch #2 on. These signals are fed to the gate 2200 by means of conductors 2748 to 2754, the conductors 2495 and conductors 2756 to 2760. The binary zero level pulse output from gate 2200 after a signal has been received is fed to the flip-flop 2454 by means of the conductor 2204 and a coupling circuit 2764. Thus, the flip-flop 2454 is cocked to allow the tape advance signal to pass through gate 2470 each time one of the latter enumerated functions is signalled from the coded tape.

When the reader and typewriter units are in the tape skip or nonprint modes and the operator actuates the stop switch 2506, it is necessary to insure that either the last code read in the reader unit has not as yet impressed a signal on the single shot multivibrator 2420, or in the alternative, insure that the pulse from multivibrator 2420 has been fed to the single shot multivibrator 2428 through the conductor 2426. This is necessary because, if a cycle through the multivibrators has been started, it is desirable that the cycle about loop 2414 be completed and the strobe and reset pulse generated before the nonprint and tape skip flip-flops 2056, 2100 are reset.

To this end, a norgate 2765 has its output fed to the resetting conductor 2228 which is connected to the reset sides of the nonprint and tape skip flip-flops 2056, 2100 (FIGURE 25). The output of gate 2765 is normally at a binary zero level due to the fact that at least one binary one signal is present at the input terminals thereof. Referring to the four input conductors, an upper conductor

2766 is connected to the reader two clutch output gate 2478 and is normally at a binary zero level due to the fact that this clutch is not used. If the reader two unit is being used, the output of gate 2478 would be at a binary zero level until such time as the 18-millisecond pulse is fed from multivibrator 2420 to advance the clutch. A second input conductor 2767 is connected to the grounding circuit 5634, to be hereinafter explained.

A third input conductor 2768 is connected to the reset side 2399 of start-stop flip-flop 2400. The reset side is normally at a binary one level until such time as the stop button is actuated to switch the conditions of flip-flop 2400 and place a binary zero level signal on conductor 2768. A fourth input conductor 2769 is connected to the output of single shot multivibrator 2428 and would normally be at a binary zero level except at such time as the multivibrator is producing an output strobe and reset pulse. It is to be noted that the signals on either of the conductors 2766, 2767 are at a binary one level at the time the signal on the conductor 2769 is at a binary zero level and the signal on the conductor 2769 is raised to a binary one level while the signal on either conductor 2766 or 2767 falls to a binary zero level. Thus the output signal of gate 2765 is inhibited until such time as all the above conditions have been met and the nonprint and tape skip flip-flops will not be reset by actuating the stop button until this time.

Referring now to FIGURES 27a and 27b, there is illustrated a timing chart which correlates the various signals generated in the writing system, one with the other, and also relates the signals to a zero time. It is to be understood that FIGURES 27a and 27b are related to one another in that the time zero for both are the same. Referring particularly to the salient points of FIGURE 27a, it is seen that the tape advance pickup signal, the signal fed to the input terminal of gate 2470, is generated at the same starting time as the reader clutch signal, the latter being utilized to set the flip-flop unit 2462. Accordingly, the input terminal from gate 2570 and the input terminal from the set side of flip-flop unit 2462 will both be at a binary zero level for a short period of time, during which the gate 2470 will generate a binary one output signal. The duration of this signal will be directly related to the duration of the tape advance pickup signal as illustrated in FIGURE 27a. At a certain point of the reader clutch signal, the reader flip-flop units will be set, as indicated by the reader flip-flop timing signal. During the period that the flip-flop units are set, a reader logic strobe signal will be generated to strobe the information from the reader flip-flops through the norgates connected thereto. The reader flip-flops will be reset in accordance with the trailing edge of the reader logic strobe signal as described in conjunction with the reader logic input circuit.

Similarly, the punch output flip-flop units will be set during a particular period of the cycle, and the punch output strobe signal will be generated during this period to strobe the information from the punch flip-flop units to the strobes connected thereto. The resetting signal for the punch flip-flops is generated during the punch output strobe signal, however, it is the trailing edge of the reset signal which actually performs the resetting signals on the flip-flop units. Referring to the punch section, the punch coil is energized during a predetermined period of the cycle, and the punch clutch is energized during the corresponding period. However, the punch clutch output signal is inhibited until such time as the paper tape contained in the punch unit has been perforated and a signal is generated in the reader control signal.

Certain other signals relating to the machine functions have been indicated such as those signals relating to the carriage return, space, upper shift, lower shift, backspace and tab, which are correlated with the signals described in conjunction with FIGURE 27a. For example, the upper shift coil is energized during a predetermined por-

tion of the cycle and the pickup coil sensing the upper shift movement generates an energizing signal at the end of the upper shift coil. The trailing edge of the upper shift coil signal starts the cycle for switching the upper shift output flip-flop unit to provide a signal to the punch unit. The other timing charts are self-explanatory in their correlation, one with the other, and it is felt that no further explanation is required for full understanding thereof.

TYPEWRITER LOGIC

As was stated above, the typewriter unit 75 is provided with a plurality of reluctance pickup units (see FIGURES 4 to 7) which sense the mechanical movement of certain operating portions of the typewriter and, through a variation in the reluctance of the gap, an output signal is generated in a coil formed about the flux path in accordance with the movement of the typewriter. Certain of these reluctance pickup units have been illustrated in the drawing which sense these mechanical movements, such as the carriage return, the back space, etc., and other reluctance pickups which are magnetically in circuit with the bails of the typewriter. Thus, as the typewriter functions are performed in addition to printing characters and numerals, a coded signal will be produced having a characteristic in accordance with either the function being performed or the particular bails being operated.

Also, certain other functions of the typewriter are sensed by means of limit switches and the like to produce an output signal in accordance with the function being performed. In still other situations, as in the upper shift and lower shift functions, a pickup coil has been provided to sense the movement of the typewriter elements performing the upper and lower shift functions. As was described in conjunction with the reader control circuit, a shift pickup coil senses the movement of the shifting of the typewriter elements and a signal is produced in accordance with the upward or downward movement of the shifting mechanism.

Certain other functions of the machine are provided merely by pushing a button such as, for example, stop code, punch off, punch on and delete code wherein a binary one level signal is fed into the input section of the typewriter logic circuitry. In this manner a particular flip-flop is operated, as will be hereinafter explained, to give an output signal which is then transmitted forward to the punch section. The tab feature of the machine may be either actuated from a key on the keyboard of the typewriter or from a rotary solenoid provided in the machine itself. The rotary solenoid is provided to allow the tab function to be performed when the machine is being operated automatically from a reader input rather than from a manual input. This provision is necessary because there is no inherent electromechanical coupling which will transform an electrical signal into the mechanical operation required, such as would be the case in the situation of the interposers and bails of the typewriter. The delete code is a similar function to the stop code, punch off and punch on in that a normal +15-volt signal is fed through a switch to an output terminal to provide a delete code signal. For purposes of simplicity, the typewriter logic will be described in the logical sequence of feeding the input signals through the logic portion and will be traced as the signals pass through the punch logic. Briefly, the input signal enters the typewriter logic system through the input flip flops and into the typewriter logic circuitry. From there, the signal is connected to a punch logic section and thence to the punch unit itself. Lastly, a punch control circuit is interconnected with the typewriter and punch logic circuit which provides the necessary control functions for the typewriter and punch logic circuit.

Machine function input circuitry

Referring to FIGURE 28 and first to the delete code, stop code, punch off and punch on functions, it is seen

75

that all of these codes are fed into the machine by means of manually operated push buttons or some other type of manual operation wherein a switching element is moved from one position to another to provide an input signal from a +15-volt source. This +15-volt source is fed through a resistor 2778 to a plurality of series switches. The first of these, a delete code switch 2780 generally comprises a movable armature member 2782 which is adapted to be moved from a normally closed position wherein the armature is in contact with a normally closed terminal 2784 thereby connecting the +15-volt source through the resistor 2778 to this terminal.

When the switch is operated to the normally open position the 15 volt source is fed to a normally open terminal 2788 and, through a conductor 2790, is fed to a norgate 2794, which then inverts this pulse signal and forms it as a square pulse. This latter pulse is fed to norgate 2796 and a positive output pulse is fed to the delete code output terminal 2798. An inhibit signal is fed from a signal producing member associated with the punch cam through a gate 2802 connected to the input side of the gate 2796. A binary one level signal is placed in the input to gate 2796 until such time as a pulse is received from the cam signal producing means. When a binary one level signal is received from the punch cam it is inverted by the gate 2802 and the inhibit signal is dropped to a binary zero thereby passing the delete code signal through gate 2796.

The +15-volt source is fed through the normally closed switch 2780 by means of a conductor 2808 to a stop code input switch 2812 which is in a normally closed position and includes an armature 2814 in contact with a normally closed terminal 2816. When the armature 2814 is moved to a normally open terminal 2820, the +15-volt signal is impressed on a flip-flop 2822 through an RC coupling circuit 2824, which switches the flip-flop to the opposite state thereby putting a binary one signal on the reset side 2826. The flip-flop has a normal state wherein a binary one level output exists at the set side 2828 and a binary zero at the reset side 2826. This binary one input signal level is fed by means of an output conductor 2830 to the stop code output terminal 2832. As was described above, a discharge resistor 2836 is provided having one terminal connected to ground to discharge the capacitor contained in the RC coupling circuit 2824. The output from terminal 2832 is fed to a patch panel, as will be seen, to punch the stop code into the tape being prepared.

With the stop code switch 2812 in the normally closed position, the +15-volt source is also fed to a punch off switch 2840 which is an identical configuration to the stop code circuitry. Thus an armature 2842 is moved from a normally closed terminal 2844 to a normally open terminal 2846 feeding the +15-volt source to a flip-flop 2850 by means of an RC coupling circuit 2852. The binary one level output of the reset side 2854 is fed to a punch off output terminal 2858 by means of a conductor 2860. Further, with the punch off switch 2840 in the normally closed position, the 15 volt source is also fed to a punch on switch 2862 by means of a conductor 2864, the switch 2862 being of identical configuration to the switches 2812, 2840.

The switch 2862 comprises a blade 2868 which is adapted to be moved from a normally closed terminal 2870 to a normally open terminal 2872 thereby feeding the 15-volt signal to the set side 2874 of the flip-flop 2876 through a coupling circuit 2880. At such time as the punch on switch blade 2868 is actuated to the normally open terminal 2872, the flip-flop 2876 is switched from a normal condition wherein a binary one level signal is present on the set side 2874 output and a binary zero is on the reset side 2882 output, to the reverse situation wherein a binary one signal from the output of the reset side 2882 is fed to a punch on output terminal 2884 by conductor 2886. A discharge resistor 2888 is provided to discharge the capacitor contained in the RC coupling circuit 2880.

As is seen from the circuit configuration of the switches,

the switches are electrically connected in series whereby, if any one switch is activated, no other switch may provide a signal to its respective flip-flop. Accordingly, if the punch off button is pushed simultaneously with the stop code button, the only signal that will be fed to its respective function flip-flop will be the stop code signal, the first switch in the series circuit from the 15-volt source. Thus, only one signal will be fed to the function flip-flops at any one time.

Referring now to the reader upper shift and lower shift functions, an output signal is derived from the upper and lower shift pickup coil 2650 which is fed to the pair of nodes 2660, 2662 respectively, as was described in conjunction with the reader control circuit 2350. These output signals are impressed on a conductor 2892 connected to the output of the first norgate 2668 from the upper shift portion and a conductor 2894 connected to the first norgate 2688 from the lower shift portion and fed to a pair of input terminals 2900, 2902 which correspond to the inputs to a pair of upper and lower shift flip-flops 2904, 2906, respectively. Referring first to the upper shift circuit, the input from the pickup coil 2650 is fed to the upper shift input terminal 2900 and thence to the set side 2910 of flip-flop 2904 by means of an RC coupling circuit 2912.

The flip-flop is switched from a binary one at the set side 2910 output and a binary zero at the reset side 2916 output to a condition of a binary zero at the set side 2910 and a binary one at the reset side 2916 output. This binary one output from flip-flop 2904 is fed to an upper shift output terminal 2920 by means of a conductor 2922. Similarly, the lower shift signal is fed to the lower shift input terminal 2902 and thence through an emitter follower 2924 and RC coupling circuit 2926 to flip-flop 2906. The signal switches the flip-flop 2906 from its normal state to the pulsed state wherein the set side 2930 goes to a binary zero level at its output and the reset side 2932 goes to a binary one output level. This binary one output is fed to a lower shift output terminal 2934 by means of a conductor 2936 as in the previous situation.

Referring next to the carriage return, space and back space functions, it is seen that these functions are provided by means of a pickup coil positioned adjacent certain mechanical portions of the typewriter to sense movement in the typewriter, as described in conjunction with FIGURES 4 to 7. Referring first to the start of the carriage return function, a pickup unit 2940 is provided which senses the beginning of the carriage return movement and feeds this pulse through a gate 2942 which amplifies and squares up the signal and thence feeds it through an RC coupling circuit 2944 to the set side 2946 of flip-flop 2948. As in the previous situations, the flip-flop is switched to the storage state wherein a binary one level output is realized at the reset side 2950, which is fed to the carriage return output terminal 2952 by means of a conductor 2954. The space function is provided by means of a space pickup 2958, the output of which is fed to a gate circuit 2960 which amplifies and squares the pulse and thence, through a RC coupling circuit 2964 is fed to the set side of 2966 of a space flip-flop 2968. The binary one output of the reset side 2970 is then fed to the space output hub 2974 by means of a conductor 2976. It will be noted that a conductor 2698 is provided whereby the output of the gate 2960 may be fed to the input circuit to gate 6072 (FIGURE 45) and then to gate 2674 in the reader control circuit 2350 by means of conductor 2700. Also, a conductor 6076 is provided from the reset side 2966 to the input of gate 6068, thereby providing an output at conductor 2700, as in the above situation. This feature is provided in order that the reader control loop 2414 may be provided with a pulsing signal to provide a continuous operation thereof. This function will be more fully described in conjunction with the description of FIGURE 45.

The back space function is similarly provided by means of a reluctance pickup 2972 wherein the signal is fed through a gate circuit 2976 and an RC coupling circuit 2978 to the set side 2980 of a flip-flop unit 2984. The output of the reset side 2986 is fed to a back space output terminal 2988 by means of a conductor 2990. An output lead 2704 is provided at the output terminal of the norgate 2976 wherein the output signal of the gate may be fed to the input of gate 2706 in the reader control circuit 2350 for a purpose similar to that described in conjunction with the space function.

As was stated above, the tab function is provided either by manual key on the keyboard or by the provision of the rotary solenoid described above. The manual button is mechanically connected to a tab switch 2996 having an armature 2998 which is in a normally closed position in contact with a normally closed terminal 3000. The armature 2998 is electrically connected to a grounding circuit through a charging capacitor 3004 and the armature 2998 is adapted to be moved to a normally open terminal 3006 which is electrically connected to a +15-volt source of power supply through a resistor 3008. When the switch is operated to the normally open terminal 3006, the capacitor 3004 is charged from the +15-volt power supply. When the switch returns to the normally closed terminal 3000, the capacitor 3004 is discharged through a diode 3010 to the set side 3012 of a tab flip-flop unit 3014 which is normally at a binary one level output on the set side 3012 and a binary zero output on the reset side 3016. A discharge resistor 3018 has been included to provide the positive potential to diode 3010.

With the input signal being fed to the set side 3012, the flip-flop unit 3014 is switched to the condition whereby a binary one output appears at the reset side 3016, this signal being fed to a tab output terminal 3020 by means of a conductor 3022. The output signal from flip-flop 3014 is also fed through an RC coupling circuit 3026 to a single shot multivibrator 3028. The output of the single shot multivibrator 3028 provides a 300-millisecond delay from the input to the output signals and this latter signal is provided to the reader control circuit for the tab signal control function through a gate 3030 and the output conductor 2694. The output signal is fed to the gate 2696 through the conductor 2694, and thence to the norgate 2674 (FIGURE 26) through the conductor 2680 to the node 2416 to provide a signal for continuously operating reader control loop. In the situation where the tabbing function is being performed but the punching unit is not operating, it is necessary that a signal be provided to reset the tab flip-flop unit 3014. To this end the output of the single shot multivibrator 3028 is fed to the gate 3030 and thence to the reset side 3016 of flip-flop 3014 by means of an RC coupling circuit 3032 and a conductor 3034.

The normal resetting signal is supplied by a grounding circuit 3040 connected to each of the flip-flop units provided in the function section of the typewriter logic input by a conductor 3042. The reset sides of the flip-flop units are connected to the conductor 3042 through a plurality of diodes 3044 to provide a blocking function after the resetting signal is terminated. The conductor is connected to the collector 3048 of an NPN transistor 3050, the emitter 3052 of which is grounded. A base electrode 3054 is connected through resistor 3056 and capacitor 3058 to a function flip-flop reset portion of the punch control circuit, as will be hereinafter explained. Thus when a signal is fed to the base electrode 3054 of the NPN transistor 3050, all of the flip-flop units connected to the conductor 3042 are grounded thereby resetting each of the flip-flop units. A resistor 3057 is connected to a -5-volts to insure the cutoff of transistor 3050.

Typewriter character input and logic circuitry

As was stated above, the typewriter units itself is provided with a plurality of reluctance pickup units which sense the mechanical movement of certain portions of elements of the machine. The reluctance pickups generally comprise a unit having an air gap in the flux path as described in conjunction with FIGURES 4 to 7 and the mechanical motion of portions of the bail system of the machine vary the reluctance of this air gap, thus producing an output signal in a coil wound on a portion of the pickup unit. As was stated above, certain of these pickup units are utilized to provide an input signal for the carriage return, space and back space functions, and it is also seen that six reluctance pickup units are provided to sense the movement of the six bail units, one reluctance unit for each bail. Thus, as the bail is operated, the corresponding reluctance pickup unit will produce an output signal which is indicative of that movement.

Referring now to the particular typewriter output logic circuits illustrated in FIGURES 29 and 30, it is seen that a plurality of magnetic pickup units 3070 to 3080 are provided, one for each of the bails of the typewriter to sense the movement thereof. As a particular bail is operated, for example bail one, the output pulse of the pickup unit 3070 is fed to a gating circuit 3084 which amplifies and squares the pulse, and the output of this gating circuit 3084 is fed to the set side 3086 of a flip-flop unit 3088 through an RC coupling circuit 3090. It is to be noted that all of the flip-flop units in the particular input section are normally at a condition wherein the output of the set side is at a binary one level and the output of the reset side is at a binary zero level. The set side 3090 output of flip-flop 3088 is fed through an emitter follower 3092 to a plurality of norgates 3094, 3096, 3098, 3100, 3102 and 3104 by means of a plurality of conductors, including a conductor 3106 and a second conductor 3108. The reset side 3110 output of flip-flop 3088 is fed through an emitter follower 3114 and a plurality of conductors including the conductor 3116 and a conductor 3118 to a further group of norgates 3122, 3124, 3126, 3128 and 3130.

Thus if a signal is received from the bail one pickup unit 3070, it is inverted through the gate 3084 and fed to the flip-flop unit 3088 by means of an RC coupling circuit 3090. It is to be noted that the RC coupling circuits will take either the positive going edge or the negative going edge of the pulse, whichever is appropriate, and will feed the output spike, in this case a positive spike, to the input of the flip-flop 3088. Thus the set of gate 3088 is switched to a binary zero output level and the reset side 3110 to a binary one. The binary zero is then fed to norgates 3094 to 3104 thereby putting binary zeroes at each of the inputs to these norgates. The binary one output from the reset side 3110 is fed to norgates 3122 to 3130.

The movement of bail two is similarly sensed by the pickup unit 3072, the output of which is fed through a gating circuit 3134 and thence to the set side 3136 of a flip-flop unit 3138 by means of an RC coupling 3140. The set side 3136 of flip-flop 3138 is fed directly to the plurality of norgates 3094, 3122, 3100 and 3126 by means of conductors 3144, 3146. The output of the reset side 3148 is fed through an emitter follower circuit 3150 to the norgates 3096, 3124, 3098, 3102, 3128, 3104 and 3130 by conductors 3152, 3154. It is to be noted that the output of the set side 3136 of flip-flop 3138 is fed directly to the norgates and no emitter follower circuit is provided in that only four norgates have been fed by this output. Contrariwise, the reset side 3148 is feeding seven norgates, therefore requires an emitter follower circuit to amplify the current of the output signal.

The movement of bail three is sensed by the pickup unit 3074, the output of which is fed to a flip-flop 3160

by means of a gating circuit 3162 and an RC coupling circuit 3164. The output of the set side 3166 of flip-flop unit 3160 is fed through an emitter follower circuit 3168 to the plurality of norgates 3094, 3122, 3096, 3124, 3100, 3126, 3102 and 3128 by means of conductors 3172 and 3174. The output of the reset side 3176 is fed directly to norgates 3098, 3104 and 3130 by conductors 3178, 3180. Again the reset side 3176 is feeding a small number of norgates and is not provided with an emitter follower circuit to amplify the current signal. Bail five is similarly magnetically connected to the pickup unit 3076, the output of which is fed to a flip-flop unit 3184 by means of a gate 3186 and an RC coupling circuit 3188. The output of the set side 3190 of flip-flop unit 3184 is fed through an emitter follower 3192 to the plurality of norgates 3094, 3122, 3096, 3124 and 3098. The output of the reset side 3196 is fed through an emitter follower circuit 3198 to norgates 3100, 3126, 3102, 3128, 3104 and 3130.

Bails five and six are sensed by means of an isolated circuit which is similar to those described above. Bail five provides a signal pulse to the pickup coil 3078, the output of which is fed to flip-flop unit 3200 by means of a gate 3202 and an RC coupling circuit 3204. The output of the set side 3208 of flip-flop 3200 is fed to a pair of norgates 3210, 3212 by a conductor 3214 and the output of the reset side 3216 is fed by means of a conductor 3220 and a second conductor 3222 to a pair of norgates 3226, 3228, respectively. Similarly, bail five generates an output signal in the pickup unit 3080 which is fed to a flip-flop 3234 through a gating circuit 3236 and an RC coupling circuit 3238. The output of the set side 3204 of flip-flop unit 3234 is fed to the norgates 3210, 3228 by means of a conductor 3242, and the output of the reset side 3244 is fed to the norgates 3226, 3212 by means of a conductor 3248.

After the information has been transferred from the bail pickup units to the flip-flop units and thence to the typewriter logic, it is necessary that the flip-flop units be reset in order to receive the next set of information bits from the operation of the typewriter. To this end a resetting signal is provided from the punch control circuit, which will be hereinafter explained. This resetting signal is fed to each of the flip-flop units 3088, 3138, 3160, 3184, 3200, 3234 by means of a conductor 3250 and a plurality of RC coupling circuits 3252 are provided between the conductor 3250 and the flip-flop units. Thus, at the proper time in the sequence of operation of the machine, a resetting signal is impressed on conductor 3250 from the punch control circuit to reset the normal conditions in the flip-flop units.

In operation, and assuming that bail one and bail four are operated, the pickup units 3070, 3076 from bail one and bail four, respectively, will receive a pulse which will be fed to each of the respective bail pickup unit output terminals. Each of these output pulses is then in turn fed through its respective gate 3084, 3186 and RC coupling circuit 3090, 3188 to the respective flip-flop units 3088, 3184. Referring now particularly to flip-flop unit 3088, it is to be remembered that the normal state of the flip-flop is wherein the set side 3086 is at a binary one level at its output terminal and the reset side 3110 is at a binary zero level. When the input pulse is received, the flip-flop unit is switched and the set side 3086 goes to a binary zero output and the reset side 3110 goes to a binary one output. The zero from the set side is fed through the emitter follower circuit 3092 and fed to the input of norgates 3094, 3096, 3098, 3100, 3102. The reset side 3110, having a binary one output, provides a signal for the emitter follower 3114 which feeds the binary one level output thereof to norgates 3122, 3124, 3126, 3128, 3130. Bail two pickup unit 3072 does not receive an input signal, therefore the set side of flip-flop unit 3138 will remain at a binary one level output and the reset side will be at a binary zero output. The binary one output is fed directly to norgates 3094, 3122, 3100, 3126.

Turning to bail three, which also does not receive a pickup signal, the set side of gate 3160 will remain at a binary one output level which is fed through emitter follower 3168 to gates 3094, 3122, 3096, 3124, 3100, 3126, 3102, 3128. Bail four does receive a pickup output and this signal is fed through the gate 3186 and the RC coupling circuit 3188 to flip-flop unit 3184, the switching of the flip-flop providing a binary zero output on the set side and a binary one output on the reset side. The binary zero output is fed through emitter follower 3192 to gates 3094, 3122, 3096, 3124, 3098. The binary one output from the reset side is fed through emitter follower 3198 to norgates 3100, 3126, 3102, 3128, 3104, 3130. Turning particularly to norgate 3098, it is seen that an input is fed from the reset side of flip-flop unit 3138 which is at a zero level due to the fact that bail two pickup unit does not receive an input signal. Also, an input to gate 3098 is fed from the reset side of flip flop 3160 which is coupled to bail three, a nonactivated bail, therefore putting a binary zero on the last input to norgate 3098.

As will be observed from the foregoing description, all of the norgates with the exception of gate 3098 have at least one, and in many instances more, binary one level inputs into them thereby giving a binary zero output at all of the gates with the exception of gate 3098. This latter gate has been provided with all binary zero inputs with the exception of one input which has not been discussed, the strobe input from the punch control circuit. Therefore, as soon as the normal binary one level signal on the strobe conductor is dropped to a binary zero level, the output at gate 3098 will go to a binary one level.

As in the above situations, the bail five and bail six pickup units 3078, 3080 do not receive an input signal and flip-flop 3200 feeds the binary one output from its set side to norgates 3210, 3212 and flip-flop 3234 from bail six feeds its set side binary one output to norgates 3210, 3228. Accordingly, each of the three norgates 3210, 3228, 3212 has at least one input of a binary one level which will give a binary zero output at each of the output terminals. However, the gate 3226 is provided, in addition to a strobe signal input, with an input signal from the reset sides of flip flops 3200, 3234. With this connection and with both flip-flops 3200, 3234 at the normal state, a pair of binary zero input signals will be provided to the input to gate 3226 to give a binary one output signal when bails five and six have not been actuated. Thus, an output signal for "none" or neither of bails five and six being actuated, is provided.

A strobe signal is fed from the punch control circuit in a manner similar to the signal generated in the reader control signal, as will be hereinafter explained. The strobe is impressed on a pair of conductors 3264, 3266, the first conductor 3264 of which feeds a strobe signal to the first eight norgates and the second conductor 3266 feeds a strobe signal to the last seven norgates. The strobe signal is so timed with respect to the operation of the typewriter machine that the signal is fed to each of the norgates at such time as all of the information in any one operation is assured of being fed through to the norgates prior to strobing these gates. In the situation where the strobe signal has not as yet been generated in the control circuit, a binary one level voltage is being fed to each of the norgates by means of the pair of strobe conductors, thus inhibiting the outputs of all of the gates. This is necessary, as in the reader circuit, in order to maintain synchronism of the signals as they pass through the logic circuitry with the operations of the machine.

The outputs of the above described norgates are fed to a plurality of output terminals in accordance with the scheme indicated on the margin of FIGURES 29 and 30. Specifically, the output of norgate 3094 is fed by means of a conductor 3270 to a norgate 3272, which then inverts the signal and impresses it on a plurality of norgates 3274, 3276, 3278, 3280 by means of a plurality of conductors 3282, 3284. These latter gates are controlled by

the signal produced from the gate 3272 and also by a plurality of signals produced from the five and six bail sections. The outputs from the five and six bail sections correspond to a sensing of bails not five and not six, bail five, bail six, and bails five and six. The outputs of norgates 3274, 3276, 3278, 3280 are fed to a plurality of output terminals 3288 to 3294 which correspond to an activation of bails one, two, three and four and a particular combination of bails five and six, as will be further explained. Thus, an output will be seen at the output terminals 3288 to 3294 each time that the first four bails are activated and produce a signal in their respective pickup coils.

Referring now to the norgates corresponding to bails five and six, it is seen that each of the norgates 3226, 3210, 3228, 3212 are connected to gates 3298, 3300, 3302, 3304, respectively, which inverts the signal and feeds the inverted signal to a plurality of output conductors 3306 to 3312 by means of emitter followers 3316 to 3322. Referring first to norgate 3226, which corresponds to an input from the reset side of flip-flop 3200 and the reset side of flip-flop 3234, it is seen that if neither flip-flop has been switched, a binary zero input is provided at both input leads to gate 3226. With two binary zeroes at the input to gate 3226, the output thereof will be at a binary one level. This binary one is fed to gate 3298 which inverts the signal and impresses a binary zero on the output conductor 3306. If either of flip-flops 3200, 3234 have been switched, a binary one will be placed on the input to gate 3226 and a binary one output will be impressed on conductor 3306 to signal this fact. Similarly, gates 3210 corresponds to a reading of both bails five and six and provides a zero output on conductor 3308 if both flip-flops 3200, 3234 have been switched. Gate 3228 corresponds to a reading of bail six and not bail five in that the reset side of flip-flop 3200 and the set side of flip-flop 3234 are connected thereto. Gate 3212 corresponds to a reading of bail five and not bail six thereby placing a binary zero on conductor 3312 when this situation occurs.

Each of the output gates 3274 to 3280 is provided with an input from the five and six bail section through conductors 3306 to 3312. The signal corresponding to neither bail five nor bail six is fed to gate 3274 from conductor 3306. Signals corresponding to a reading of bail five, bail six and bail five and six are fed to gates 3276 to 3280 by means of conductors 3312, 3210, 3208, respectively. Thus a signal at terminal 3288 corresponds to a reading of bails one, two, three and four. Similarly, an output at terminals 3290 to 3294 corresponds to a reading of the above four bails plus bail five, bail six and bails five and six.

Norgate 3122 is similarly connected to a gate 3326 and the output of gate 3326 is connected to a plurality of gates 3328, 3330, 3332, 3334 which invert the signal and produce an output at a plurality of output terminals 3336 to 3342. Gates 3328 to 3334 are also provided with signals from conductors 3306, 3312, 3310, 3308 corresponding to signals from the five and six bail gates. Accordingly, the output terminals 3336 to 3342 correspond to an activation of bails two, three, four and the respective combinations of bails five and six. Gate 3096 is connected to a gate 3346 which inverts the output therefrom and the output of gate 3346 is impressed on a plurality of gates 3348 to 3354 in addition to the signals on conductors 3306, 3312, 3310, 3308. The outputs of these latter gates are fed to a plurality of output terminals 3356 to 3362, one connected to each of the gates and a signal at these output terminals corresponds to a signal from bails one, three, four and the respective combinations of bails five and six.

The norgate 3124 is connected to a plurality of output terminals 3368 to 3374 through a gate 3376 and a plurality of gates 3378 to 3384 corresponding to outputs of three and four of the first four gates. Similarly, the gates 3098, 3100, 3126, 3102, 3128, 3104 and 3130 are connected to a plurality of inverter gates 3388 to 3400 and a plurality of groups of output gates 3402 to 3408, 3410 to

3416, 3418 to 3424, 3426 to 3432, 3434 to 3440, 2442 to 3448 and 3450 to 3456 which combine the various outputs from bails one to four with the outputs from bails five and six. The outputs of gates 3402 to 3456 are fed to a plurality of output terminals 3460 to 3514, respectively. These output terminals produce binary one output signals in accordance with the particular bails actuated as indicated along the right side and bottom of FIGURES 29 and 30. All of the other output terminals will be at a binary zero output level.

Continuing the description of the operation and particularly referring to gate 3098, all of the inputs thereto are at a binary zero level thus giving a binary one output, this latter output being inverted by means of gate 3388. This binary zero signal is fed to the gates 3402 to 3408 which also has an input to each gate corresponding to neither bail five or six being activated which will provide a binary zero input to gate 3402, a reading of bail five only to provide a binary zero input to gate 3404, etc. Assuming neither bail five nor six was energized, a pair of binary zero outputs will be impressed on gate 3402 to give a binary one output signal at output terminal 3460. Each of the bail five and six input conductors 3312, 3310, 3308 will have a binary one signal level on them to provide a binary zero level output signal at each of the output terminals 3462 to 3466. Thus the outputs corresponding to gate 3098 at terminals 3462 to 3466 will have binary one level inputs at the bail five and six input conductors 3312, 3310, 3308, therefore giving a binary zero output. It is seen that only one terminal of all the output terminals will have a binary one output and all of the other terminals will be at a binary zero output. The same is true whether a five or a six or a five and six signal is read from the five and six bails. In this situation, if a five is read, the output will appear at the second terminal; if a six is read the output will appear at the third terminal, and if a five and six are read the output will appear at the fourth terminal of the proper four terminal group. Thus the typewriter logic has taken the six inputs from the bail pickup coils and transformed them into forty-four outputs which reflect forty-four possible combinations of the activations of the bails. These forty-four output combinations are necessary to achieve the letter and numeral characteristics of the preferred typewriter machine described.

PUNCH LOGIC

The bails of the typewriter machine are activated according to a particular code which is peculiar to the machine being utilized. This code is directly related to the position of the keys of the machine and when a particular key of any machine is activated, a certain sequence of bails will be energized to give an output at one of the forty-four output terminals described above or a particular machine function reluctance pickup unit is energized. Certain of these machines differ, one from the other, in that certain keys have been interchanged, that is, where a particular letter is interconnected with a particular set of interposer rods on one machine, another letter may be interconnected with that same set of interposer rods on another machine. Thus, if any particular interposer rod on the machine is activated, the same output terminal will be energized for that particular rod. Thus, for a majority of prior art machines, if a particular key is punched, for example, the second key of the second row, a particular sequence of bails will be energized irrespective of what letter is connected to that key, and the same output will always be present at a particular output terminal.

Referring now to FIGURES 31, 32, 33 and 34, it is seen that the various outputs from the forty-four output terminals of the typewriter logic and the other output terminals from the typewriter function pickup units are connected to the hubs of a patch panel 3516 contained within the program board 590. These connections are

made in accordance with a particular scheme which is related to the positions of the keys on the keyboard, as will be hereinafter explained, and these latter outputs are patched to a punch logic circuit 3518.

A patch panel 3516 has been provided, partially shown as a double row of hubs 3520, 3522 which may be utilized for patching the output of the typewriter logic section, FIGURES 29 and 30, with the punch logic section 3518 and also to conduct signals to other portions of the circuitry. Each of the hubs has been numbered in accordance with its respective decimal equivalent for the particular sequence of bails and, while only one hub has been illustrated for each number, it is to be understood that a plurality of hubs are provided for each decimal number. The hubs have been numbered according to a decimal number sequence which is equivalent to the corresponding binary digit of the seven binary channels thereby giving 128 hubs numbered from decimal 0 to decimal 127. The outputs of the hubs are fed into the punch logic section in accordance with the particular decimal number assigned to both the hub and the input conductors.

The binary numbering sequence has been chosen in accordance with the binary to decimal conversion table of the type wherein the decimal equivalent is equal to the factorial of the binary number as is well known in the art. For example, a decimal 127 is equivalent to a reading of a binary one in all seven channels and a decimal 85 is equivalent to a binary one reading in channels one, three, five and seven. Inputs to a decimally numbered patch panel are fed to a plurality of input terminals 3526, 3528 (FIGURE 33) which have been arranged in two banks depending on whether the connection is to a decimal number of 64 or greater, which is fed into a first set 3526 of input terminals or the number is a connection of 63 or less in which case it is connected to a second set 3528. While only the first 64 hubs (decimal 0 to 63) are required, it will be seen that the system has been adapted to be utilized with an eight channel tape wherein the first six channels are in accordance with the factorial of the binary number. The seventh channel is obtained by adding a binary one to the repeated system of the first six channels (FIGURES 33 and 34) of input terminals of the punch logic circuitry. Also provisions have been made to punch a code in the eighth channel, as will be hereinafter explained.

The first set 3526 of input terminals is connected through a plurality of interconnected conductors, generally designated 3530, to a first set of input norgates 3534 to 3562 which are of the type described above, that is producing a binary one output with all of the inputs to the gate being at the binary zero level or producing a binary zero output when any one or more of the inputs are at a binary one level. The gates are of the double or triple input type wherein only one load resistor is used for two or three gate circuits to accommodate a group of more than five inputs. The second set of input terminals 3528, those connected to the decimal 63 hubs 3520 and below, are connected to a second set of norgates 3568 to 3594 which are of the identical type as described in conjunction with the first set of input terminals 3526. The connection between the input terminals 3528 of the lower numbered set are made to the gates 3568 to 3594 by means of a plurality of conductors 3596, as illustrated in FIGURES 32 and 33.

Referring first to the low numbered input norgates of FIGURES 32 and 33, it is seen that a binary one signal on any of the input terminals 3528 will be fed to the gates 3568 to 3594, thereby producing a binary zero output at that particular gate. This output signal is fed to a second series of gates 3600 to 3626 which inverts the binary one signal to a binary zero output level. It is to be noted that all of the other gates in the series will have a binary one output at their output terminals due to the consistency of the zero inputs at the input terminals to

the gate. The outputs of the gates 3600 to 3626 are fed to a plurality of six norgates 3630 to 3640 corresponding to the first six channels of the punch unit. The inputs corresponding to the decimal 0 to 63 hubs are interconnected to energize the proper output punches in accordance with the binary equivalent of the decimal number being punched. The outputs of gates 3630 to 3640 are fed to a plurality of six inverter gates 3640 to 3650 which invert the binary zero signal to a binary one, thereby indicating the pulsing of a particular channel of the punch unit.

Referring to the first norgate 3568, it is to be noted that all of the decimal inputs to the gate require an indication in channel one of the output punch unit. Accordingly, the output from the first gate 3568 is fed to the input of the gate 3600 corresponding to channel one of the output punch unit. Thus the decimal one is fed to the channel one output gate 3630 and the input for decimal nine is fed to both norgates 3568 and 3582 to provide an output in channels one and four, or a binary equivalent of decimal nine. The inputs to the norgates 3568 to 3594 have been chosen in accordance with the particular outputs required. For example, if a particular decimal number requires an output in channels one and three, such as decimal five, the input will be provided at norgate 3576 which is connected to output gates 3630, 3634 corresponding to channels one and three. Decimal thirteen also requires an output in channels one and three and further requires an output in channel four. Thus decimal thirteen is also fed to norgate 3582 which provides an input to channel four. The norgates 3600 to 3626 are interconnected with output gates 3630 to 3640 as shown.

Referring now to the output circuit for channels one to six, the output of gate 3640 is fed to the set side 3658 of a channel one flip-flop unit 3660 through an RC coupling circuit 3662. The flip flop unit 3660 is normally at a binary one level at its output terminal on the set side 3658 and a binary zero level at the output terminal on the reset side 3664. If a binary one level input signal is fed to gate 3630, its output terminal will go to a binary zero, this output being inverted by gate 3640. The positive pulse is fed to flip-flop 3660, thereby switching the flip-flop unit to provide a binary zero level output signal at its set side 3658 and a binary one on its reset side 3664. The output of flip flop unit 3660 is fed to a norgate 3668 which produces a binary one signal at its output terminal. This binary one signal pulses a driver circuit 3670, the output terminals 3672 of which is connected to the driver coil of the channel one output punch.

When the punch coil is energized by a signal from gate 3668, the punch will perforate the tape and provide an indication in channel one of the tape. A plurality of other inputs are provided for gate 3668 as will be hereinafter explained, but for the present it will be assumed that each of these inputs are at a binary zero in order to provide a binary one output at the output terminal of gate 3668. The discussion of these inputs will be reserved until such time as a complete discussion of the punch control circuit is provided. Also, the outputs from the set side from the flip-flop unit 3660 is fed through a conductor 3674 and a cable 3676 to an auxiliary output channel one which is connected to an auxiliary punch unit, illustrated in FIGURE 41.

Similarly, the output of norgate 3632 is fed gate 3642 which inverts the signal and feeds it through an RC coupling circuit 3680 to the set side 3682 of a flip-flop unit 3684. The output of flip-flop 3684 is fed to gate 3686 in a manner similar to that described above, and the output of gate 3686 is impressed on a driver unit 3688 which activates the coil of channel two of the punch unit. Similarly, the rest of the norgates 3644 to 3650 are connected to the set sides 3692 to 3698 of flip-flop units 3700 to 3706, respectively, through a plurality of RC coupling circuits 3708 to 3714. These latter flip-flop units 3700 to 3706 provide outputs in channels three, four, five and six of the punch unit by means of a plurality of norgates

3720 to 3726 and a plurality of driver circuits 3728 to 3734 to a plurality of output terminals 3736 to 3742.

The above description of the operation of the second group of norgates 3568 to 3594 is applicable to the first

5 six punch units insofar as the sixty-four inputs may be fed to no less than six channels. In order to obtain the seventh channel the upper sixty-four decimal numbers (64 to 127) have been fed to the first group of norgates 3534 to 3562 which are so interconnected with the second

10 group of norgates 3568 to 3594 as to give an output in all of the seven channels in accordance with the common and well known binary to decimal conversion table. For example, the decimal number 19 corresponds to an

15 output in channels one, two and five for the first six channels and the corresponding number in the seventh channel would be decimal 83 wherein a one would be punched in channel 7. Thus, the table is developed from 0 to 63 for the first six channels and from 64 to 127 by adding a bit in channel seven and repeating the table for the first

20 six channels. In order to obtain the output in the seventh channel, the circuitry has been developed whereby a decimal number in the higher order will produce an output which is identical to its decimal number in the lower order plus an output in channel seven.

25 As was stated, the upper set of numbers from 64 to 127 requires an output in channel seven and accordingly, the norgate 3562, a fifteen input gate for channel seven, is provided wherein certain of the input terminals are connected to the channel seven norgate 3562 by

30 means of a plurality of conductors 3746. It is to be noted that the channel seven bit is provided in two different modes, the first being by feeding the information to gate 3562 prior to feeding the same information to gates 3534 to 3560 and the second by sensing the outputs of these

35 3534 to 3560 and the second by sensing the outputs of these latter gates. As an example of the first mode, decimal 88 has its signal fed to both gates 3552 and 3562 simultaneously while, as an example of the second mode, decimal 89 has its signal fed to gate 3552 and 3534 and the output of gate 3534 is fed to gate 3750, then to 3562. The outputs of the plurality of norgates 3534 to 3560 are fed to a second plurality of norgates 3750 to 3776 which inverts the signal and feeds the output thereof to the set of norgates 3568 to 3594 discussed above.

Specifically, the output of gate 3750 is fed to the input of gate 3568 by means of a conductor 3780 and the output of gate 3752 is fed to the input of gate 3570 by a conductor 3782. Similarly, the outputs of gates 3754 to 3776 are fed to the inputs to gates 3572 to 3594 by means of conductors 3784 to 3806. As an example, an input at

40 the decimal 73 input terminal 3522 will be impressed on gate 3568 through gates 3534, 3750 and conductor 3780 to give an output in channel one of the punch unit. Also, the signal is fed into gate 3582 through gates 3548, 3764 and conductor 3794 to give an output in channel four of the punch unit. The output of gate 3750 is also fed

45 down to the channel seven gate 3562 through one of the conductors 3746. With a binary one appearing on one of the conductors 3746, the output of gate 3562 is switched to a binary zero level which is fed to an inverter gate 3810 which produces a binary one output signal. The signal is fed through a conductor 3812 to a gate 3814 which

50 inverts the signal and feeds it to a second gate 3816. The binary one signal from gate 3816 is fed to the set side 3818 of flip-flop unit 3820 through an RC coupling circuit 3822.

providing an output in channel seven is included in the system of feeding an input to gate 3562 directly from the input terminals 3522. As is seen from the drawings, certain of the decimal hubs 3522 are connected to the inputs to gate 3562 which inverts the signal giving a binary zero output at the output terminals thereof. This output is in turn fed to gate 3810, as described above, which is then fed directly to the gate 3814 to give an output in channel seven.

To further describe the circuit by way of operation, it is seen from the table illustrated in FIGURE 24 that the letter "a" corresponds to an actuation of bails three, four and five which will provide an output pulse at output terminal 3370 (FIGURE 29) of gate 3380. Assuming that an "a" is punched in a paper tape, the coded output would appear as a hole in channels one, five and seven. A decimal number which would correspond to this output would be at the decimal 81 terminal, thereby giving the proper output signal at the punch unit. An input to the decimal 81 input hub 3522 will produce a binary one signal at the input to gates 3534, 3550 and 3562, the last being the gate providing a channel seven output. This binary one signal provides a binary zero output at the output terminals of the norgates 3568 and 3584, which are in turn fed to gates 3630, 3638, respectively.

A binary zero also appears on the output terminal of gate 3814 and a binary one will appear on the output terminal of gate 3816 which is fed to flip-flop 3820, thereby providing an output in channel seven. The input to gates 3630, 3638 provides a binary zero output at the output terminals which is fed to the input to gates 3640, 3648 thereby giving a binary one output at the output terminals of gates 3640, 3648. The binary one output from gate 3640 is fed to flip-flop 3660 to provide a binary one output to switch the flip-flop 3660. The binary zero output of the set side of flip-flop 3660 is fed to gate 3668 which energizes the driver 3670 to provide an output in channel one of the punch unit. The output from gate 3648 is fed to the set side 3696 of flip-flop unit 3704. The output of the set side of flip-flop unit 3704 is fed to gate 3724 which energizes the driver 3732 thereby giving an energization of the coil of channel five in the punch unit.

From the foregoing description, it is seen that a seven channel tape may be punched from the logic provided and further provisions have been made to provide an eight channel output where desired. To this end, a plurality of four norgates have been connected together to provide a single gate 3850 having twenty input terminals to include an output in channel eight. With a signal from the typewriter logic which is desired to be put into an eight channel tape, it is necessary that the output signal be fed both to the typewriter logic, described above, and additionally to one of a plurality of input hubs 3852 to gate 3850. With this paralleled output provision, the normal seven channel output will be provided and also a bit will be punched in the eighth channel of the tape by means of an input signal fed to a gate 3856 through a conductor 3858 from a gate 3860. The output of gate 3856 is fed through a conductor 3862 to gate 3864 and, if the eighth channel is desired to be punched, a binary one input will be fed to gate 3856. The output of gate 3864 is fed to the set side 3868 of flip-flop unit 3870 through an RC coupling circuit 3872. The output of flip-flop unit 3870 is fed to a gate 3876 which inverts the binary zero to a binary one and feeds it to a driver unit 3878 associated with the coil of the channel eight punch unit.

An inhibit function has been provided to inhibit the outputs of all of the output gates 3600 to 3626 and gate 3860 whenever it is desired that the particular punch unit is not to be used. To this end a ground circuit 3884 is connected to a +15-volt source of electrical energy by means of a conductor 3886 and a punch on-off switch 3890 is connected in series therewith. When the switch is opened or in the punch "off" position, the base-emitter input is taken off the ground unit 3884, thereby switching

the NPN transistor contained therein to the nonconductive state. With the NPN transistor in the nonconducting state, the node at the output of the grounding unit 3884 is at a binary one level, thereby putting a binary one level signal on a pair of conductors 3892, 3894 through diodes 3896, 3898. This signal is fed through the diode and conductors to each of the gates 3600 to 3624, 3860, thereby putting a binary one voltage at the input terminals thereof and a binary zero output at its output terminal. Also, the binary one signal is fed by means of a conductor 3900 and a diode 3902 to the norgates 3750 to 3776 to inhibit the outputs of these output gates. Further, the output of gate 3860 is inhibited by placing the binary one signal on the input terminal thereof to inhibit the channel eight output. When the switch is closed, the grounding circuit is conductive to ground the node 3902 and thus remove the inhibit signal from the above described conductors.

An inhibit function is provided for the output gates 3600 to 3626 and 3860 from the set side 2066 of the nonprint flip-flop 2056 in the reader section (FIGURE 25). A binary one signal is fed from flip-flop 2056, through the conductor 2084 and a conductor 3910 to a diode 3912 and a pair of emitter follower circuits 3914, 3916 to conductors 3892, 3894. Thus an inhibit signal is fed to the inputs of the lower decimal output gates 3600 to 3626 and 3860. This signal is also fed by means of an emitter follower 3920 to inhibit the output gates 3750 to 3776 and 3810 of the higher decimal section by means of conductor 3900. Similarly, an inhibit signal is fed from the format control system punch off-punch on flip-flop, as it will be hereinafter explained when the format control portion of the system is described.

The set of gates 3630 to 3640, 3814 and 3856 are provided with an additional input by means of a plurality of conductors 3924 to 3938 which are connected to the output terminals 1480 of the reader nonprint gates described in conjunction with the typewriter input logic (FIGURE 22). This feature has been provided in the event that it is desired to punch a portion of coded tape without having a page printed by the typewriter. Accordingly, when the nonprint signal is fed from the typewriter logic section to the input terminal 2052 and thence to the reset side 2054 of flip-flop 2056 by means of gate 2070 and RC coupling circuit 2072, an output is received at the conductor 1488 connected to the emitter follower unit 2116. This output signal is fed to the gates 1460 to 1474 of the reader nonprint output section, thereby providing a binary one at the output terminals 1480 thereof.

The output terminals 1480, as stated above, are connected to the inputs of the gates, described above, by means of conductors 3924 to 3938 to provide an actuating signal for each channel of the punch unit. It is to be noted that gate 1474 is connected to conductor 3924 of gate 3630 (channel one), gate 1472 to gate 3632 (channel two), etc. Accordingly, if a particular channel is energized in the reader input logic section by means of the reader itself, the signal is fed from the set side of its respective flip-flop unit to the particular channel output gate and this output is fed directly to the input of a gate connected to that same channel in the punch section. Thus, if a signal is read in channel eight and it is desired to reproduce this signal in the punch section without providing a printed page, the signal is fed directly from the channel eight output terminal 1480 to the input of the channel eight norgate 3856 and thence to the flip-flop unit 3870 and out to the channel eight punch unit.

If none of the channels have been read and the unit is in nonprint or some other function which does not produce a printed page, a binary zero is provided which is generated by feeding the inputs of the not one, not two, and not three bits, the not four, not five and non six bits and the not seven and not eight bits to the input of the gate 1484 (FIGURE 22). Thus a signal will be produced at the binary zero output terminal 1482 when none of the channels have been punched in the tape being read by the reader section, and this output is fed to the input

conductor 3944 to gate 3946 (FIGURE 35), for a purpose to be hereinafter described.

A reset signal is provided from the punch control circuit (FIGURE 35) to reset each of the flip-flop units 3660, 3684, 3700 to 3706, 3820 and 3870. The binary one reset signal is impressed on a conductor 3950 which is connected to the reset sides 3664 and 3952 to 3964 through a plurality of RC coupling circuits 3968. Thus, after the information has been passed from the flip-flops to the punch output gates, the flip-flops are reset to receive the next set of information. This operation is maintained in synchronism with the remainder of the system as will be seen in conjunction with the description of the punch control circuit.

PUNCH CONTROL CIRCUITRY

The operation of the above described typewriter logic circuit and punch logic circuit are controlled for a great part by a punch control circuit 4000 which is similar in operation and function to the reader control circuit 2350. The punch control circuit 4000 is a system which performs generally the same function as the reader control circuit, that is, to provide a strobe signal for the output norgates in accordance with a particular synchronism which is developed in time sequence with the operation of the reader, and to advance the punch clutch as was the situation in the reader section wherein the reader clutch was advanced. As was stated in conjunction with the reader control circuit, the power turn on sets all of the flip-flop units including the flip-flops of the punch section to the start or normal condition. Accordingly, a set signal to set the flip-flop units in the punch section is not required to be generated in the punch control circuit 4000. However, the punch control unit provides a resetting signal for the bail flip-flops described in conjunction with the typewriter logic and punch output flip-flops of FIGS. 33 and 34 and also to reset the function flip-flops of the typewriter logic circuit. Thus, the punch control circuitry provides substantially the same control functions as was provided in the reader control circuit. A correlation of the initial condition set pulses of the reader control circuit are illustrated in the timing chart of FIGURE 36.

As in the situation with the reader control circuit, the continuous operation and synchronism of the punch control circuit is dependent on the receipt of a signal indicating the storage of information to be advanced to the output circuit, in this case, the punch unit itself. In order to accomplish this function, the output from the punch flip-flop units are fed from the reset sides 3664 and 3952 to 3964 into a pair of norgates 3946 and 4001 by means of a plurality of conductors 4002 connected to the reset sides 3958 to 3964, the conductors forming cable 4004. A plurality of conductors 4008 from the reset sides 3664 and 3952 to 3956 are joined with cable 4004 to form cable 4012 which feeds input signals to the gates 3946, 4001. It is to be noted that the reset sides will have a binary one output at their output terminals when the flip-flop unit has been switched by receiving a signal at its input terminal. Thus, when any one of the channels of the punch unit has been actuated, a binary one input will be fed to norgates 3946, 4001 thereby giving a binary zero at its output terminal.

When the situation occurs that none of the channels have been activated, a binary one input signal is fed from the binary zero hub 3516 (FIG. 31) to an input conductor 4016 thereby providing an indicating signal when none of the channels are to be punched for any bit and the punch clutch is to be advanced. In this situation, a particular lack of bail operations will provide an output at the output terminal 3508 connected to gate 3450, this signal being attached to the binary zero hub which is in turn attached to the binary zero input conductor 4016 to gate 3946. Also, a tenth input is provided to the gates 4001, 3944 from the binary zero nonprint gate

1484 in the reader input logic section (FIG. 22). These various ancillary inputs, such as binary zero punch input and the binary zero nonprint gate input, are provided where none of the punch output flip-flop units have been activated to produce a binary zero input at all of the other eight inputs to gates 3946, 4001. In order to provide the proper control functions from the punch control circuit, it is necessary that an input be fed to the gates 3946, 4001 each time the punch clutch is to be advanced one step even though a zero or no reading is obtained in any of the eight channels of the punch unit.

The output from the norgates 3946, 4001, which are illustrated as a single output gate having ten inputs, is fed to a control circuit link 4120 by means of a conductor 15 4122 and a norgate 4124. With a zero input on the other input terminal 4126 of gate 4124, as will be hereinafter explained, a binary one output will be impressed on the output terminal of gate 4124. This binary one output is fed through an RC coupling circuit 4128 to a single shot multivibrator unit 4130, which activates the multivibrator, and provides an output at its output terminal with approximately a ten millisecond delay inherent therein. This output pulse is fed through an RC coupling circuit 4132 to a second single shot multivibrator 4134 which provides an output pulse having an additional three to five millisecond delay to include sufficient delay in the strobe and reset signals when in the nonprint mode or the select/all mode, to be described later. The output pulse from multivibrator 4134 is then fed through an emitter follower unit 4138 to a gate 4140 which inverts the pulse to a zero output pulse, which is fed in turn to norgate 4144 by means of a conductor 4146. Norgate 4144 also has an input signal fed thereto by means of a conductor 4148 from the output terminal of a flip-flop 4150 in the select/all circuit illustrated in FIG. 38 and to be described in conjunction with the description of that figure. For the present it will be assumed that the signal on conductor 4148 is at a binary zero level as is the signal on conductors 4154, 4156 connected to the parity check circuit.

Referring back to the input to norgate 4144 it is seen that a fourth input is provided by means of a conductor 4174 which is connected to the skip-stop flip-flop 2100 through emitter follower 2106, diode 2192 and conductor 2194. When a signal is passed to flip-flop 2100, thereby placing a binary one signal at the output terminal thereof, an inhibit signal is fed to the gate 4144 to inhibit the operation of the punch control circuit link 4120. With this inhibit signal being fed to gate 4144, the operator is allowed to skip tape through the reader unit without providing an output signal to the various channels of the punch unit.

The output of gate 4144, a binary one when all binary zeros are present on the input conductors is fed to an inverter gate 4160 which inverts the signal to a binary zero level and feeds it to the set side 4162 of a flip-flop 4164 through an RC coupling circuit 4166. The initial conditions in flip-flop 4164 are set by the grounding circuit described in conjunction with FIG. 26 wherein the output of gate 2392 is fed to the reset side 4170 of flip-flop 4164 through a conductor 4172 and an RC coupling circuit 4173. When the power is initially turned on in the grounding circuit 2352, a pulse is fed to gate 2392 which causes the output thereof to go to a binary zero level, thus putting an input pulse to flip-flop 4164. This signal from multivibrator 2386 is utilized to completely set the punch circuitry and also has an inherent delay to ensure that the punch control circuit is in the set condition after the reader section has been set. The output of the set side 4162 of the flip-flop unit 4164 goes to a binary zero level and the reset side 4170 is switched to a binary one level when the flip-flop is pulsed. The set side output is fed through an emitter follower circuit 4180 to an output norgate 4182. The input circuit of gate 4182 is also connected by

means of a conductor 4184 to a punch inhibit circuit which provides an inhibit signal from the output of the punch off circuitry in the machine function reader section. When the punch inhibit signal is at a binary zero and not inhibiting, the pulse through gate 4144 will be inverted by gate 4160 and a binary one pulse will then be fed to the punch clutch through a driver circuit 4186 and a conductor 4188.

Referring back to the machine function portion of the reader logic section in FIGURE 25, a punch operation circuit 4190 is provided which receives an operating signal to turn punch one on, punch two on or turn one or both punches off. To turn punch one on, a signal is impressed on an input terminal 4192 which feeds the signal to the set side 4194 a flip-flop unit 4196 through a diode 4198 and an RC coupling circuit 4200. The flip-flop is normally set at a condition where its set side 4194 is at a binary one output level and the reset side 4204 is at a binary zero output level. After the pulse has switched the condition of the flip-flop 4196, a binary zero output signal is fed to the conductor 4174 connected to the inputs to gates 4124, 4144 for the inhibit purpose described above, through an emitter follower circuit 4206.

The signal is also fed to a conductor 4208 connected to the plurality of gates 3668, 3686, 3720 to 3726, 3824 and 3876 (FIGURES 25, 26) to provide an inhibit function when it is not desired to use punch one. This signal is fed from conductor 4802 to the conductor 4182 to inhibit the punch clutch output gate 4182 when this punch unit is not being used. When it is desired to turn the punch units off, a signal is fed to the punch off terminal 4212 (FIG. 25) connected to the reset side 4202 of the flip-flop 4196 through an RC coupling circuit 4214. A binary one pulse at terminal 4214 will reset flip-flop 4196 and place an inhibit signal on the output terminal at the set side of flip-flop 4196. A punch two on flip-flop 4218 is provided with an input signal at punch two terminal 4220 through an RC coupling circuit 4246.

The flip-flop 4218 is normally at a binary zero on the output of the reset side 4226 and a binary one at the output of its set side 4228. The set side 4228 is connected through a conductor 4230 and an emitter follower 4232 to an auxiliary punch strobe circuit 4234 (FIG. 33). The strobe circuit is connected to an auxiliary punch unit illustrated in FIG. 40 and comprises a gate 4236 having a plurality of inputs including an inhibit signal from conductor 4174 in the tape skip mode, a strobe signal from the punch control circuit, a parity check inhibit signal from the parity check circuit and the signal from conductor 4230. The output of gate 4236 is inverted by an inverter gate 4238 and fed to the auxiliary punch circuit by means of an emitter follower 4240 and an output conductor 4242.

Referring back to FIG. 25, it is to be noted that the punch off signal from terminal 4212 is also fed to the reset side 4226 of flip-flop 4218 by means of a conductor 4244 and an RC coupling circuit 4222. Thus the punch two on flip-flop 4218 is reset by the same signal as reset the punch one on flip-flop 4196. If it is desired to turn one of the two punch units off when both are running, it is necessary to turn both punch units off with the signal from terminal 4212 and then turn the single desired punch unit back on by a signal at its respective terminal 4192, 4220. The flip-flops 4290, 4196, 4218 are initially set by the setting signal on conductor 1962 which is impressed on the flip-flops through a plurality of diodes 4250.

Referring to FIG. 35, a strobe signal is fed to the output norgates 3668, 3686, 3720 to 3726, 3824, 3876 of the punch unit by means of a conductor 4276 connected thereto to strobe the information contained therein to the coils of the various channels of the punch unit. As the punch clutch is actuated, a punch pickup reluctance coil 4278 will sense the progression of the punch clutch through a particular angle and provide an input signal at

the punch reluctance unit 4278 at a preselected point of advancement and feed this binary one signal to a gate 4280 connected thereto. The output of the gate 4280 is fed to a second gate 4282 by means of a conductor 4284 which inverts the binary zero output pulse from the gate 4280 to a binary one pulse. This latter pulse is fed through an RC coupling circuit 4286 to the reset side 4170 of flip-flop unit 4164 thereby switching the flip-flop unit 4164 to a binary one at the set side 4162 output terminal and a binary zero at the reset side 4170, thereby resetting flip-flop unit 4164. The binary zero output from the reset side 4170 of flip-flop 4164 is also fed to a norgate 4290 which provides a resetting function for the punch output flip-flops and other flip-flop units, as will be now explained.

The binary one output from norgate 4124 is fed to a second single shot multivibrator 4292 by means of an RC coupling circuit 4294 and a conductor 4296 to provide an output pulse from the multivibrator 4292, which is an eighteen millisecond pulse. The output of the multivibrator 4292 is fed by means of a conductor 4298 to a gate 4300 which inverts the signal and feeds a binary zero to a gate 4304 by means of a conductor 4306. The gate 4304 also has a second input conductor 4310 which is connected to the inhibit punch flip-flop 4150, on the set side 4312 thereof, from the select/all circuit of FIG. 38, as will be hereinafter explained.

The flip-flop unit 4150 (FIG. 38) in the select/all circuit is normally at a binary zero at its reset side 4314 and a binary one at its set side 4312. This binary one signal is fed into gate 4304 (FIG. 35), thereby giving a binary zero output at its output terminal. The binary zero output is fed by means of a conductor 4316 to the gate 4290 which has an input on conductor 4320 from the reset side 4170 of flip-flop unit 4164 due to the resetting action of the punch pickup coil and the gate 4290 also has a binary zero input from conductor 4174 connected to the reader tape skip unit, as described above. The final input terminal 4324 to the norgate 4290 is connected by means of a conductor 4326 to the ground circuit 2352, which is normally at a zero level with the exception of the time just after the power is initially turned on. Thus the binary one output from gate 4290 is fed to a plurality of sections of the system, for example, the function flip-flops (FIG. 28) and bail flip-flops (FIGS. 29 and 30) of the typewriter logic section, the punch inhibit flip-flop 4150 in the select/all section and the output flip-flops in the punch logic section (FIGS. 33 and 34) by a conductor 4330.

The reset signal is fed to the punch output flip-flops by means of an emitter follower 4332 and the conductor 3950 connected thereto. Similarly, the bail flip-flops in the typewriter logic section are supplied with a reset signal by an emitter follower 4336 and the conductor 3250 and the reset signal for the inhibit flip-flop 4150 is fed by means of a conductor 4338 and an RC coupling circuit 4340. Also, the signal to reset the function flip-flops is fed by means of a conductor 4344 and an emitter follower 4346. The latter signal is fed to the base 3054 (FIG. 28) through resistor 3056 and capacitor 3058 by means of terminal 4348. Thus, with all of the inputs of gate 4290 at a zero level a binary one level will be realized at its output, which is fed to reset all of the flip-flop units described above.

As was described in conjunction with the description of FIGS. 29 and 30, it is necessary to strobe the information stored in gates 3094 to 3104, 3122 to 3130, 3210, 3212, 3226 and 3228, and the pair of strobe conductors 3264, 3266 have been provided for this purpose. The conductors 3264, 3266 are connected to a strobe flip-flop unit 4350 (FIG. 35) at the set side 4352 thereof. The flip-flop 4350 is normally at a condition wherein the set side 4352 is at a binary one output level and the reset side 4354 is at a binary zero level. This binary one signal is fed to the strobe conductors 3264, 3266 by a

pair of emitter followers 4356, 4358 which boost the current signal to a level which will accommodate the plurality of gates and the signal will inhibit these gates until such time as the flip-flop has been switched. The flip-flop 4350 is switched by a signal received from the print shaft pickup unit 2574 in the reader section, the signal being impressed on the set side by means of a conductor 4360 and an RC coupling circuit 4362. The switching of flip-flop 4350 places a binary zero level signal on strobe conductors 3264, 3266 from the set side 4352 while a binary one signal from the reset side 4162 of flip-flop 4164 inhibits the outputs to the punch clutches by placing the binary one signal into the input terminals of gate 4182 and an auxiliary punch clutch output gate 4366 through an emitter follower 4368 and a conductor 4370. Thus, the output signal to the punch clutch is inhibited while the typewriter logic is strobed to preclude spurious signals from activating the punch clutch.

The flip-flop 4350 is reset each time by the signal generated from the reset gate 4290 as it is fed through emitter follower 4346 and the conductor 4344 to the function flip-flops. This signal is also fed to the reset side 4354 of flip-flop 4350 by means of a conductor 4372 and an RC coupling circuit 4374. The circuit is initially set by an RC coupling circuit 4378 connected to the grounding circuit illustrated in FIG. 26 by means of the conductor 2390. When the power is initially turned on, a binary one pulse is fed to the reset side 4354 to initially set the conditions of the flip-flop 4350. It is seen that the auxiliary punch clutch gate 4366 is also provided with a punch number two inhibit signal from the function inputs of FIG. 25, over conductor 4230 (FIG. 33) and thence to the input to gate 4366 by means of a conductor 4384. In this way the output of the auxiliary punch unit is inhibited by precluding the advancement of the auxiliary punch clutch.

The punch clutch output driver circuit 4186 is provided with a grounding switch 4386 including an armature 4388 which is adapted to be moved from a normally open position in contact with a normally open terminal 4390 to a normally closed position in contact with a closed terminal 4392. The other end of the armature is grounded through a conductor 4392 and, when the armature is moved to the position in contact with terminal 4392, a continuous ground is placed on the collector electrode of the NPN transistor contained in the driver 4186. Thus, when it is desired to pass tape through the punch unit without punching any coded information therein, as in the situation where a lead or tail is being placed on the tape, the switch 4386 is actuated to provide a continuous current through the punch clutch coil. As soon as the switch 4386 is released the action of the punch clutch will stop and the circuit will be ready to receive coded information.

AUXILIARY SYSTEM FEATURES

Select/all circuitry

In certain applications utilizing the system of the present invention, it is desired that certain characters or machine functions will not be printed or punched or will not be punched. The select/all circuit illustrated in FIGURE 38 provides a function whereby certain input signals read in the reader unit and placed through the reader input logic circuitry may either bypass the typewriter input logic and the punch logic thereby merely reading tape through the tape reader and not producing an output in the page of the typewriter unit or the tape in the punch unit, or certain other signals may be selected to be page printed with the typewriter but deleted from the punch unit output, or in the third case wherein certain other select signals from a third group are deleted from the punch unit while being printed on the typewriter. To achieve this first situation wherein the reader unit reads the coded tape but it is decided both to bypass the typewriter unit and the punch unit, the signal is fed di-

rectly from the reader logic output hubs 1100 to 1119 to a plurality of input hubs 4400 of the nonprint inhibit norgate 4402.

The output of this gate produces an output of a binary zero level at the output terminal of the norgate 4402. The output of the gate is fed to a second gate 4406 which inverts the signal and feeds it to the set side 4312 of the flip-flop unit 4150 by means of a conductor 4408 and an RC coupling circuit 4410. The flip-flop unit 4150 is normally at a binary zero output level on its reset side 4314 and a binary one level on its set side 4312. The reset side of flip-flop unit 4150 is connected by means of the conductor 4148 to the input of norgate 4144, as described above. With the binary one input level being fed thereto after the flip-flop 4150 has been switched, the output of gate 4144 will go the zero level which will inhibit the pulse being fed from gate 4140 through gate 4144 to gate 4160. With the norgate 4144 at the zero state on its output terminals, the output of the single shot multivibrator 4134 to flip-flop unit 4164 is blocked and the punch clutch will not be advanced nor will a strobe shot be fed to the output norgates in the punch unit.

However, the set side of the flip-flop 4150 is fed to the gate 4304 as described above, putting a binary zero input at the input terminal to that gate and ready to receive the binary zero going pulse from the gate 4300, which is pulsed from the multivibrator 4292. With both inputs to the gate 4304 at a binary zero level, a binary one will be provided at its output terminals and fed to gate 4290. With one of the input terminals of gate 4290 at a binary one level, a binary zero output will be realized thereby producing a zero going pulse to the reset circuits. The trailing edge of the zero pulse is utilized to reset the output flip-flops to the punch unit by means of the reset conductor 3950 and reset emitter follower 4332. Also the bail flip-flops and punch inhibit flip-flop are reset through emitter follower 4336 and the function flip-flops are reset through emitter follower 4346. Thus the inhibit punch flip-flop unit is reset each time the bail flip-flop units are reset and the punch control circuit is ready to receive the next bit of information from the punch unit output flip-flops.

The "all" feature of the circuit provides a capability of selecting certain of the outputs from the decimal output hubs in the punch logic circuitry and feeding these signals to flip-flop unit 4150 of FIGURE 38 when the particular signals are desired to be deleted from the punch unit.

In this situation, the input signals are fed to a plurality of input terminals 4420 which in turn feed the signal to a gate 4422. The output from gate 4422 is fed by means of a conductor 4424 to a norgate 4426 which has a second input terminal connected to a select/all switch 4430. When the input is realized on an "all" input terminal, a binary zero output is fed to the gate 4426 on one input terminal thereof. The select/all switch generally comprises an armature 4432 which is adapted to be moved between a plurality of positions in contact with a "select" terminal 4434, an "all" terminal 4436 and a select/all terminal 4438.

The armature 4432 of the switch 4430 is connected through a resistor 4440 to a +15 volt source of DC power supply connected to a terminal 4442. By selectively engaging one of the terminals, either select/all or select or all, the respective gate may be inhibited from passing its output to the flip-flop 4150. If the "all" mode is selected, then the switch will be moved to the "all" position 4436 thereby removing the +15 volt signal from an input conductor 4444 to gate 4426, thus the output thereof will be at a binary one level and this signal will be fed to the flip-flop unit 4150 through an RC coupling circuit 4446 and a conductor 4448. With the positive pulse input to the set side of the flip-flop unit 4150, the flip-flop will be switched thereby putting a binary one on the output of the reset side and a binary zero on the output

of the set side. These signals are fed to the punch control circuit as described above.

Similarly, the "select" mode involves feeding one of the selected signals to a plurality of select input terminals 4452 from certain preselected decimal output hubs. The signal from the decimal output hub is fed through a gate 4454 and thence through a third gate 4456. With the switch 4430 in the "select" position, the inhibit signal will be removed from the gate 4456 and a pulse will be fed to the flip-flop unit 4150 through an RC coupling circuit 4458. With the switch in the "select/all" position, the inhibit voltages will be removed from both gates 4426, 4456 and any signals which have been programmed into either the "all" or the "select" gates will be fed through to the flip-flop unit 4150 to effect a control of the punch control circuit. These features have been provided to enable the operator to delete certain codes from the punch unit and the typewriter unit in the case of the non-print inhibit mode and to delete other codes from the punch unit only in the all, select or select/all mode.

Parity check circuit

In order to check the correctness of the output signals being fed to the punch unit, a parity check circuit 4460 illustrated in FIGURE 39 has been provided, which checks the parity of the output signal in accordance with a preselected combination of output signals being fed to a gate circuit. As is well known in the use of an eight channel circuit, it is possible to have 256 combinations of those eight channels whereby 256 different bits of information may be transmitted. Of these 256 combinations, 128 will comprise bits in an even number of channels, thus a reading in for example, channels 1, 2, 3, 4, 5, 6, 7 and 8, or channels 1, 2, 3, 4, 5, 6, 7 and 8. Also 128 combinations will have an odd number of bits in any piece of information, that is wherein one channel, three channels, five channels or seven channels have been punched. In a scheme such as that described, it is possible to choose either even or odd 128 combinations, and check the output of the circuit to assure that either the even or the odd combinations are being passed through the system. Thus, if an odd code has been chosen and an output is received at the print section which comprises a reading in channels 1, 2, 3, 4, 5, 6, 7 and 8, it is seen that an error has occurred in the system.

In order to check this possibility of an error occurring, wherein the error comprises a signal being received in the output punch unit which is of the opposite parity from that of the chosen code, a parity check circuit 4460 has been devised and connected to the output terminals of the punch unit. The input for the parity circuit is derived directly from the output terminals of the output flip-flop units of the punch unit, and this output is fed to a plurality of parity input norgates. The signal is passed through a series of interconnected norgates and the output thereof is chosen as to whether it is to be an even parity check or an odd parity check. This output is fed to the output norgates in the punch unit to provide an inhibit signal at such time as the parity proves to be wrong. If the parity checks out as expected, then a binary zero is put onto the input inhibit conductors of the norgates and the output signal from the flip flop units is passed to the punch coils.

The parity output signal is also fed to the punch control unit to inhibit the punch control functions thereof thereby precluding the possibility of advancing the punch clutch and strobing the erroneous output signal from the output norgates. The parity signal further provides a signal to a keyboard lock mechanism whereby the keyboard is locked to preclude any further information from being manually fed into the typewriter machine. Thus the parity signal inhibits the output of the erroneous information, inhibits the punch control circuit to eliminate a strobe and a punch clutch signal grounds the start button switch circuit in the punch control circuit and also provides a signal to lock the keyboard of machine to preclude any fur-

ther information from being fed thereto. The signals generated in the operation of the parity check circuit are illustrated in the timing chart of FIGURE 37.

Each of the output flip-flop circuits in the punch output unit is provided with a pair of output terminals 4462 to 4476 and 4478 to 4492 which are connected to the set and reset sides, respectively, of the output flip-flops in the punch logic. The output signals are fed to the input terminals of the parity circuit by means of a plurality of pairs of conductors, as indicated in FIGURE 39. Referring particularly to the parity circuit 4460, it is seen that a plurality of input nand gates are provided, 4500 to 4514 wherein each of the gates is provided with a pair of input terminals which receive the output signals as indicated from the respective flip-flop units in the punch logic circuit. The parity check circuit logic has been evolved in accordance with the well known Boolean algebra process. Thus, by writing the equation for all of the possible odd parity codes and reducing the equation to its simplest form, the following equation is obtained:

$$P_{\text{odd}} = [(5 \oplus 7) \oplus (1 \oplus 3)] \oplus [(8 \oplus 6) \oplus (4 \oplus 2)]$$

Similarly, the even code equation is written and resolved to its simplest form by the same process to obtain the equation:

$$P_{\text{even}} = \overline{[(4 \oplus 2) \oplus (8 \oplus 6)] \oplus [(1 \oplus 3) \oplus (5 \oplus 7)]}$$

From the foregoing equations, the following parity check circuit is derived to enable the user to check either odd or even parity.

For example, nand gate 4500 receives the output signals from the reset sides of channels two and four and nand gate 4502 receives the outputs from the set sides of channels two and four. Gates 4504, 4506 receive the outputs from the reset sides of channels six and eight and the set sides of channels six and eight, respectively. The lower half of the circuit is identical in configuration and is provided the inputs from the odd channels, as for example, gates 4508, 4510 are provided with the outputs from the reset sides of channels one and three, and the set sides of channels one and three, respectively. Similarly, gates 4512, 4514 are provided with the output signals from the reset sides of channels five and seven and the set sides of channels five and seven, respectively. This particular configuration of input gates has been devised to provide a single output for an even parity check, and this even output is inverted by an inverter gate to provide an output for the odd parity.

The outputs of gates 4500, 4502 and 4504, 4506 are fed to a pair of norgates 4520 and 4522, respectively, by two pairs of conductors 4524, 4526, respectively, and the output of gate 4520 is fed to an inverter gate 4528 and a nand gate 4530 by means of a pair of conductors 4532, 4534. The output of gate 4522 is fed to the nand gate 4530 by a conductor 4536 and a second inverter gate 4538 by a conductor 4540. The outputs of gates 4528 and 4538 are connected to a nand gate 4544 by means of a pair of conductors 4546, 4548 and the outputs of 4544 and 4530 are fed to a norgate 4550 by means of conductors 4552, 4554.

On the odd channel side, the circuit configuration is identical in that the outputs of nand gates 4508 and 4510 are fed to a single norgate 4558 and the outputs of nand gates 4512 and 4514 are fed to a single norgate 4560. The output of gate 4558 is fed to an inverter gate 4562 and a nand gate 4564, and the output of gate 4560 is fed to the same nand gate 4564 and a second inverter gate 4566. The outputs of gates 4562 and 4566 are fed to a single nand gate 4568 and the outputs of gates 4564 and 4568 are fed to a norgate 4570.

The output of gate 4550 is fed to an inverter gate 4574 and a nand gate 4576 by means of a pair of conductors 4578, 4580 and the output of gate 4570 is fed to the same nand gate 4576 and an inverter gate 4582 by means of a pair of conductors 4584, 4586, respectively. The outputs

of gates 4574 and 4582 are fed to a single nand gate 4590 and the outputs of 4576 and 4590 are consolidated to a single norgate 4592 by means of a pair of conductors 4594, 4596.

If an even code has been utilized in the system, the parity check is taken from the output of gate 4592 by means of a conductor 4594 and the signal is boosted through an emitter follower circuit 4596 giving an output signal at the even output terminal 4598. If the parity check is correct, then a zero output will appear at the even terminal and will not inhibit any of the gates described above. If an odd code is being utilized in this system, then this latter output signal must be inverted and this is accomplished through a gate 4600 the output of which is amplified by an emitter follower circuit 4602 to give the odd output at an odd output terminal 4604. A switch 4608 (FIG. 33) is provided to close the circuit between the output terminals 4598, 4604 and an output parity inhibit conductor 4610 feeding this signal to the respective output gates in the punch control circuit, the switch 4608 having an armature 4612 which is adapted to engage the terminals 4598, 4604 to conduct the output signal to the parity circuit. A third open circuited terminal 4613 is provided in the event the user does not wish to have a parity check. It is to be understood that the parity check circuit may be patched directly to the conductor 4610 by selectively providing a patching conductor to a hub connected thereto.

As was stated above, the output signal from the parity circuit 4460 is fed to the plurality of output gates which, if an incorrect parity is sensed, will inhibit the output signal of the flip-flop units from being passed through the output logic. As was further stated above, the punch control circuit is activated by a signal from the reset side of the output flip-flop units. In order to inhibit this signal from passing through the punch control circuit and thus advancing the punch clutch and generating a strobe signal, the parity check signal is also fed directly to the punch control circuit by means of the conductor 4145. This parity signal is fed to the gate 4144 thereby inhibiting the signal from the single shot multivibrator 4134 from passing through gate 4144. However, the pulse from the single shot multivibrator 4292 will pass through its normal circuitry giving an output pulse to emitter followers 4336 and 4346 from gate 4290 to reset the bail flip-flops and the punch inhibit flip-flop and also to reset the function flip-flops, in that the parity signal will not impair the operation of this portion of the circuit.

In describing the operation of the parity circuit, assume that channels two, four, five and six have received signals to punch the outputs in those channels. In this situation, the set output side of flip-flop 3660 will be at a binary one level and the reset side will be at a binary zero, the set side of flip flop 3684 will be at a binary zero and the reset side output will be at a binary one, and the set side of flip-flop 3700 will be at a binary one and the reset side will be at a binary zero. Similarly, the set side of each of flip-flops 3702, 3704, 3706 will be at a binary zero level output and the reset side output will be at a binary one level. Similarly, the set output sides of flip-flop units 3820 and 3870 will both be at a binary one output and the reset sides will both be at a binary zero.

Each of these outputs are fed by means of the conductors 4462 to 4492 to the input side of the nand gates as indicated by the numerals placed adjacent the output leads and the input terminals, the two matching in their number configuration. By considering an output in channels two, four, five and six, it is seen that the code chosen for the system is an even code if the output signal in channels two, four, five and six is correct, or on the other hand, if the signals are incorrect then an odd code has been chosen. It will be assumed for exemplary purposes, that an even code has been chosen and the checking of this code will be described by following the signals through the parity check circuitry.

The input to gate 4500 corresponds to the $\bar{2}$ and $\bar{4}$ output terminals and accordingly, a binary one on each of these input leads will be realized to give a binary zero output at the output terminal of gate 4500. The gate 4502 has signals impressed thereon from the 2 and 4 output terminals which are both at a binary zero level thereby giving a binary one at the output terminal of gate 4502. The zero signal from gate 4500 and the binary one signal from gate 4502 are fed to gate 4520 thereby giving a binary zero output at its output terminal. This zero output is fed to both gates 4528 and 4530 giving a binary one output at gate 4528. Referring back to gate 4504 it is seen that the input terminals correspond to the signals from the $\bar{6}$ and $\bar{8}$ side which have a binary one and a binary zero level input signal, respectively. Thus a binary zero output is realized at the output terminal of gate 4504.

Also, gate 4506 corresponds to the 6 and 8 output which have a binary zero and a binary one signal fed thereto producing a binary zero output at the output terminal of gate 4506. The two binary zero signals are fed from gates 4504 and 4506 to gate 4522 giving a binary one output signal at its output terminal. This binary one output is fed to gate 4538 giving a binary zero at its output terminal and to gate 4530. With the binary one at the input terminal to gate 4530 and a binary zero at its other input terminal, a binary zero output will be realized at this gate. Also, the output from gate 4528, at a binary one level, is fed to the input to gate 4544 and the zero output from gate 4538 is also fed to gate 4544. With both gates 4544 and 4530 having a binary one level signal being fed to the inputs thereof, both output terminals will be at the binary zero level which is fed to gate 550, giving a binary one at its output terminal.

Referring now to the odd numbered channels receiving signals from the punch output flip-flop units, it is seen that the gate 4508 has a pair of binary zero level signals fed to the inputs thereof corresponding to a $\bar{1}$ and $\bar{3}$ being read at the flip-flops. With a binary zero at both of the inputs to gate 4508, a binary one is fed at the output terminal to the gate 4558. Also, gate 4510 has a pair of input signals corresponding to a reading in channels 1 and 3, giving a binary zero output at its output terminal. The binary one output from gate 4508 and the binary zero output from gate 4510 provide a binary zero output at the output terminal of gate 4558. This zero output is fed to gate 4562 which boosts its output terminal to a binary one level and the output of gate 4558 is also fed to gate 4564. Gate 4512 has a binary one and a binary zero input corresponding to the signal level at the output terminals of the flip-flops of the $\bar{5}$ and $\bar{7}$ signals, thereby giving a binary zero output at its output terminal.

Also gate 4514 has a binary zero and a binary one at its input corresponding to a 5 and a 7 signal, also giving a binary zero at its output terminal. The two binary zero outputs are fed to the input of gate 4560, giving a binary one at its output terminal. This binary one is fed to gate 4566 which produces a binary zero at its output terminal and to gate 4564 which produces a binary zero at its output terminal. The output from gate 4566 is fed to the input of gate 4568 and coacting with the binary one at the input thereof, a binary zero output is realized at the output terminal of gate 4568. The binary zero output from gate 4564 and 4568 are combined in gate 4570 to produce a binary one output at its output terminal.

The output from gate 4550 is fed to gate 4576 and to gate 4574, giving an output at the binary zero level at this latter gate output terminal. Also gate 4570 has its output fed to gate 4576 putting a binary one at its input therein and a gate 4582, the latter gate inverting the signal and producing a binary zero at its output terminal. The input to gate 4576 produces a binary zero 75 at its output terminal and the outputs from gate 4574

and 4582 are fed to gate 4590, both input signals being at the binary zero level, thereby producing a binary one output at the output terminal of gate 4590. The outputs from gates 4576 and 4590 are fed to the gate 4592 which produces a binary zero at its output terminal due to the binary one output from gate 4590.

As was stated above, if it is desired to choose an even code and check the parity thereof, the output from the parity circuit will be taken directly from the output terminal of gate 4592. From the above description it is seen that the output of gate 4592, when 2, 4, 5 or 6 channels have been read, is at a binary zero level. This binary zero is fed by means of the conductor 4594 and emitter follower circuit 4696 to the even parity output terminal 4598 which is at a binary zero level. This binary zero level signal is fed to the input terminals of the output norgates through the punch program board or the switch 4608. A noninhibit binary zero signal is produced whereby the information may be passed through the output norgates if the other inhibit signals are at a binary zero level and a strobe signal is produced. Also the zero parity check signal is fed to gate 4144 which produces a binary zero signal at the input to gate 4144 and also the signal is fed to a gate 4620 for a purpose to be hereinafter explained.

Assuming that either the switch has been inadvertently placed on an odd parity check or the odd parity output has been patched when an even parity code is being utilized or an odd parity code has been chosen and the output signals from the punch output flip-flops has been received as described above, the reading of 2, 4 5 or 6 channels will produce a binary one level signal at the odd parity output terminal 4604 and if an odd parity code is being utilized this signal will obviously be in error. This error signal is fed by means of the conductor 4610 to the punch output norgate units to put a binary one signal on one of the input terminals thereof. Thus, all of the punch output norgates are inhibited and the information from the output flip-flop units will not be passed to the punch unit. Also, this binary one signal from the odd parity check terminal 4604 is fed to gate 4144 thereby inhibiting the operation of the punch control circuit and eliminating the possibility of a strobe signal and a punch clutch signal being generated and also the signal is fed to the gate 4620 (FIGURE 35). This binary one signal into gate 4620 will produce a binary zero at its output terminal which is in turn fed to a norgate 4622 by means of a conductor 4624. The single shot multivibrator 4292 is connected by means of a conductor 4628 to one of the input terminals of gate 4622 and this conductor will normally be at a binary one level output until such time as the single shot multivibrator 4292 is triggered. A third input to gate 4622 is provided from the single shot multivibrator 4134 through emitter follower 4138 and a conductor 4630. This conductor is normally at a binary zero level and thus puts a binary zero on the input to norgate 4622 until such time as the multivibrator 4134 is triggered.

Looking at the three input terminals to gate 4622, it is seen that the output from gate 4622 is at a binary zero level, the input from single shot multivibrator 4292 being at the binary one level and the input from the single shot multivibrator 4134 being at the binary zero level. At the same instant of time, single shot multivibrators 4292 and 4130 are triggered and the input terminal from the single shot multivibrator 4292 will immediately go to a binary zero level. However, at this instant of time, the input terminal receiving a signal from the multivibrator 4134 will remain at a binary zero level, thus the signal levels on the lower two input terminals to gate 4622 will be at a binary zero level. These binary zeros will remain on the input to gate 4622 until such time as the pulse from multivibrator 4134 is fed to the gate 4622.

Thus, all of the inputs to norgate 4622 will be at a binary zero level for the next ten milliseconds until the termination of the shot from multivibrator 4292. During this ten millisecond period the output of gate 4622 goes to a binary one level which is fed to the set side 4632 of a flip-flop unit 4634 through an RC coupling circuit 4636. This output from gate 4622 is also fed to the reader clutch (FIGURE 26) by means of a conductor 4638 to inhibit the operation of the reader clutch by placing a binary one signal on the input to gates 2476, 2478. The signal on conductor 4638 is also fed to a grounding circuit 4637 by means of a conductor 4639. The grounding side of the grounding circuit 4637 is connected to the input to flip-flop 2400, in the reader start circuit, by means of a conductor 4641 to thereby ground the input to this gate. In this way, the user may not start the reader circuit by actuating the start button inasmuch as the input to the start-stop flip-flop 2400 is grounded. The grounding circuit also receives an input from the program home circuit by means of conductor 4143 to also ground the start-stop flip-flop 3400 input circuit to preclude the operator from actuating the start button during the period in which the system is homing, to be hereinafter explained. The input pulse on conductor 4143 is also impressed on node 2416 through an RC coupling circuit 4145. Thus, the control loop 2414 is energized. The input signal on conductor 4143 is further fed to gate 2399 by means of conductor 4147, thereby producing a binary zero at the input terminal to gate 2450.

With the signal being fed to flip-flop 4634, the set side 4632 will go to a binary zero output signal level and the reset side 4640 will go to a binary one output level. The binary one signal is fed by means of a conductor 4642 and an emitter follower circuit 4644 to a driver unit 4648 which is connected to a keyboard lock solenoid 4650. The keyboard lock solenoid operates to lock the keyboard by any suitable method (not shown) to preclude the user from feeding signals into the system manually. The output signal from the reset side of flip-flop 4634 is also fed to the stop flip-flop circuit 2400 (FIGURE 26) in the reader section by means of a conductor 4652 and RC coupling circuit 4654 to stop the operation of the reader control circuit in a manner similar to the action of pressing the stop button 2506. Thus, the operation of the reader control circuit is stopped by the signal on conductor 4652 and may not be restarted by means of the start switch 2504 due to the grounding effect of the grounding circuit 4637.

The single shot multivibrator 4292 has been activated by gate 4124 due to the fact that the action of the punch output flip-flops has not been deterred by the parity circuit and therefore a reset signal is passed through gates 4300, 4304, 4290 to reset the bail flip-flops and punch inhibit flip-flop and also the function flip-flops. Also the signal is fed to emitter follower 4332 to reset the output flip-flops of the punch output circuit. Similarly, the signal from emitter follower unit 4336 is fed by means of a conductor 4658 and an RC coupling circuit 4660 to the keyboard lock flip-flop 4634 to reset the flip-flop after the erroneous signal has been received. This reset is delayed due to the inherent delay achieved in the single shot multivibrator 4292.

With the foregoing parity check circuit, it is seen that any error which may occur in the output flip-flop circuits to the punch unit will be detected and the feeding of these outputs will be blocked by an inhibit signal fed to the output norgates, thereby precluding the punching of the erroneous signals. Also, the parity circuit is seen to provide a reset signal for all of the flip-flop units which has been set by the erroneous signal and the reader has been advanced to the next bits of information. Moreover, the parity check circuit is provided with a feature wherein the keyboard of the typewriter unit is immediately locked to preclude the operator from feeding further signals into

the typewriter in the manual operation. This locking of the keyboard is released by merely turning the on-off switch to off position and then turning the switch to the on position. When this operation is completed, all of the flip-flop units normally set by the turning on of the power supply will be set, as described above.

Data feed control circuits

Referring now to FIGURE 40, there is illustrated an auxiliary punch circuit which is utilized in conjunction with the punch control circuit 4000 in a manner similar to the use of that circuit with the main punch unit and the punch logic output flip-flops 3660, 3682, 3700 to 3706, 3820 and 3870. The outputs of the set side of the latter flip-flops are fed by means of conductors (FIGURES 33 and 34), which form a cable 3676, to an auxiliary punch unit 4670. The conductors of cable 3676 are adapted to be connected to a plurality of input hubs 4672 to 4686, which correspond to the input terminals for channels 1 to channel 8, respectively. A binary one signal being fed to the input hubs 4672 to 4686 are fed to a plurality of input norgates 4688 to 4702, these latter gates having a plurality of four inputs thereto. The first of these inputs is the input conductor for the signal from the punch unit output flip-flops and the second is a strobe conductor 4704 which is adapted to be connected to the auxiliary punch outputs strobe, parity and punch inhibit conductor 4242 illustrated in FIGURE 33.

Thus with each of the input conductors to gate 4236 at the binary zero level, including the conductor 4230 from FIGURE 25, a binary one output will be realized at the output terminal thereof which is inverted by gate 4238 and impressed on conductor 4242. As the particular circuit is illustrated, it is to be understood that the strobe conductor 4704, a parity inhibit conductor 4706 and a punch inhibit conductor 4708 are all interconnected and fed by the signal from the conductor 4242. However, it is to be further understood that these three input signals may be separated and fed from separate sources to provide a further control over the auxiliary punch circuit. In the particular circuit illustrated, the signal on the punch inhibit conductor 4708 corresponds to the signal received from FIGURE 25 on conductor 4230 and the parity inhibit conductor 4706 corresponds to the parity inhibit signal received on conductor 4154 (FIGURE 34).

An auxiliary punch clutch driving unit 4710 is illustrated as being attached to the punch clutch coil 4712 which is actuated when a signal is fed from the auxiliary punch clutch gate 4366 (FIGURE 35) to an auxiliary punch clutch input terminal 4714. Thus each time the punch clutch is advanced by a signal generated in the punch control circuit 4000 and the auxiliary punch is on thereby putting a binary zero signal on conductor 4384, the punch clutch 4712 will be advanced. As in the situation with the punch clutch pickup unit 4278 for the main punch, a similar pickup unit 4718 is provided which senses the punch movement and sends a binary one signal to a gate 4720. This gate 4720 inverts the signal to a binary zero and feeds it to a second gate 4722 which in turn inverts the signal and feeds a binary one level signal to an output terminal 4724. This latter terminal 4724 is connected to an input terminal 4726 in FIGURE 35 wherein the binary one signal generated by the pickup unit 4718 is fed to the reset side 4170 of flip-flop 4164 by means of RC coupling circuit 4728. Thus the operation of the punch control link 4120 is continuously operated as though the main punch unit were being operated.

The signals being produced at the output terminals of gates 4688 to 4702 are fed to a second row of gates 4730 which inverts the signal and feeds it to the drivers 4732. The output of these latter drivers are fed to the punch coils 4734-4748 corresponding to the punch coils in channels one to eight respectively. Thus by providing a signal to the proper flip-flop unit, either punch one on flip-flop 4196 or punch two on flip-flop 4218, either of the punch

units may be controlled from the punch logic circuitry and the punch control circuit.

Data card feed control circuit

Referring now to FIGURE 41, there is illustrated a schematic diagram of an edge card feed unit which is adapted to be connected to the reader unit and may be used in association with a data storage device feed apparatus such as that described in application Ser. No. 352,232, filed Mar. 16, 1964. FIGURE 42 illustrates a punch unit card feed circuit which may be associated with apparatus such as that described in the foregoing patent application and the circuit is adapted to be interconnected with the system described above. With a system incorporating the edge card portion for the reader, a user may provide a plurality of punch cards having information coded therein and, by feeding these punch cards to the edge card reader unit, the reader described above will sense the information stored on the card and pass this information on to the system. Thus, a page print may be produced from a punched card and an identical punch card may be produced in the punch unit or a tape may be produced from the punched card. Thus the versatility of the foregoing system is greatly increased in that the data storage capabilities of the system are enhanced by the use of punch cards. The punch cards are easily storable and may have information typed thereon to enable the user to readily ascertain the coded information contained on the card by merely reading the card.

Referring first to FIGURE 41, there is illustrated an edge card circuit which is adapted to be controlled by a card passing through the edge card mechanism (not shown) associated with the reader unit. The circuit 4760 generally comprises a flip-flop unit 4762 having a set side 4764, which is normally at a binary one output level, and has a conductor 4766 connected to grounding circuit 5634 (FIGURE 26) by means of a conductor 4766. The binary one signal on this output conductor inhibits the operation of the reader clutch connected to conductor 2496, by means of the grounding of the output signal on conductor 2496 through the action of ground circuit 5634, thereby turning the reader off. The flip-flop unit 4762 has a reset side 4770 connected to the node 2416 in FIGURE 26 by means of a conductor 4772 and an RC coupling circuit 4774. Thus each time the flip-flop 4762 is switched to put a binary one output level on the reset side, the control loop 2414 (FIGURE 26) in the reader circuit will be actuated to provide a reader clutch activating signal and a strobe signal. The initial conditions of the flip-flop units 4762 are set by the set circuit in FIGURE 26 wherein the conductor 4326 is connected to the reset side 4770 by means of an RC coupling circuit 4778. Thus on initial power turn on, a positive pulse is received at the reset side to set the output level of the reset side to a binary zero and thereby setting the output level of the set side to a binary one level.

When a card is initially fed through the mechanism described in the foregoing patent application, a rear switch 4780 is engaged, the switch having an armature 4782 in contact with a normally open terminal 4784 and adapted to be moved in contact with a normally closed terminal 4786. When the armature has been actuated to the normally closed position, a +15-volt power supply is fed from a terminal 4788 through a resistor 4790 and the armature 4782 to a conductor 4792. A norgate 4794 is illustrated as being connected to the conductor 4792 by means of a diode 4796 and the gate 4794 is shown as having a pair of input conductors 4798 and 4800. The conductor 4798 is connected to the input conductor 2492 to norgate 2476 which normally has a binary zero on this conductor due to the fact that this reader unit is normally actuated. The second input conductor 4800 is connected to the output of the emitter follower unit 2546 which also has a binary zero on the output thereof at such time as the power has been turned on and the reader switch has been actuated

to the "on" position. Thus, it is only necessary that the power be turned on and the reader "on" switch actuated to produce a pair of binary zero level inputs to gate 4794.

However, prior to this condition, if a card should be passed through its card mechanism, the 15-volt signal passing through resistor 4790 and switch 4780 would be shunted by means of diode 4796 through the conducting transistor of gate 4794. At such time as the gate 4794 is turned off or the transistor contained therein is turned off by a pair of binary zeros at its input base circuit, the signal from the 15-volt power supply will pass through a resistor 4804 to produce approximately a 15-volt potential at conductor 4792. This 15-volt potential is fed to set side 4764 of flip-flop 4762 by means of an RC coupling circuit 4806. This binary one lever signal will switch the flip-flop unit 4762 to a binary zero output at the set side 4764 and a binary one level signal at the output of the reset side 4770. Thus the inhibit is removed from the input to gate 2476 by conductor 4766 and a binary one signal is fed to the node 2416 to cause the control loop 2414 to cycle, thereby producing a reader clutch output signal to advance the reader clutch.

As the edge card is being passed through its card reader mechanism, the card will engage a front switch 4810 having an armature 4812 which is adapted to engage a normally closed terminal 4814 and a normally open terminal 4816. When the armature is moved into contact with terminal 4816, a capacitor 4820 is charged from the 15-volt power supply at terminal 4788 through a resistor 4822. This capacitor 4820 is maintained in the charged condition until such time as the trailing edge of the card releases the switch 4810 thereby allowing the armature to come in contact with terminal 4814 and placing a binary one level pulse into the reset side 4770 of flip-flop 4762. The current signal to the reset side 4770 is passed through a resistor 4826 to ground and to diode 4828 thereby producing approximately a binary one potential at the input to the diode 4828, thus triggering the flip flop 4762.

When the flip-flop 4762 has been switched back to its normal state by receiving a pulse through switch 4812 from capacitor 4820, the signal on conductor 4772 will drop to a binary zero level thereby eliminating the signal to the node 2416 and also the signal on conductor 4766 will rise to a binary one level thereby inhibiting the gate 2476 and turning the reader clutch off. It is seen that a plurality of cards may be successively passed through the reader unit without disengaging or releasing the switch 4810 thereby successively feeding the card through the mechanism and reading the information coded thereon. In this way a very large number of coded cards may be processed to produce a page print, a punch tape and/or a punched card and greatly facilitating the processing of the information thereon.

As illustrated in FIG. 42, the edge card punch circuit 4840 is adapted to be connected to the punch control circuit to control the output pulses to the punch clutch. Also the circuit contains an output hub which is adapted to be interconnected with the delete code hub in the machine function input logic section illustrated in FIGURE 28 to punch a delete code when it is desired to merely pass the card through the punch section. Accordingly, the edge card circuit 4840 generally comprises a flip-flop unit 4842 having a set side 4844 which is normally at a binary one level at its output terminal and a reset side 4846 which is normally at a binary zero at its output terminals. The set side of the flip-flop 4842 is connected through a gate 4850 to an output hub 4852 through a diode 4854, the output hub 4852 being connected to the punch clutch input circuit, as illustrated in FIGURE 35. With the set side 4844 normally at a binary one level at its output terminal, the punch clutch is not actuated due to the inversion of this binary one signal by the gate 4850.

The initial conditions of the flip-flop 4842 are set by means of a signal impressed on a conductor 4860 which is connected to the ground circuit described in conjunction

with FIGURE 26 such as, for example, by a connection to conductor 4326. In the situation where the reader unit and control circuitry is not being used, that is, where the information to be put on the punch card is to be fed into the system by manually typing on the typewriter unit, the initial conditions of the flip-flop 4842 are set by means of a conductor 4860 and an RC coupling circuit 4862 where are connected to the punch on-off switch 3890 illustrated in FIGURE 34 and controlled thereby. Thus when the switch 3890 is closed, a 15-volt pulse will be fed through the RC coupling circuit 4862 to the reset side 4846 and thereby setting the reset side at the initial binary zero condition at its output conductor. Accordingly, the true side 4844 will go to a binary one level at its output conductor.

When a card is initially fed into the card mechanism mounted on the punch unit, the card will first engage a front automatic card feed limit switch 4866 and actuate an armature 4868 thereof from a position in contact with a normally closed grounded terminal 4870 to a position in contact with a normally open terminal 4872. The terminal 4872 is connected to a positive 15-volt source of power supply to a resistor 4874, and, upon the engagement of the armature 4868 with the contact 4872, a binary one pulse is fed to the set side of flip flop 4842 through an RC coupling circuit 4876 and a conductor 4878. When the card depresses the switch, the flip-flop 4842 will be at a switched condition wherein the set side is at a binary zero at its output terminal and its reset side is at a binary one at its output terminal. This binary zero is inverted by the gate 4850 and fed to the punch clutch through diode 4854 and output terminal 4852. Thus the punch clutch would be advanced.

As is seen from the foregoing copending application, the card is so designed as to have provided therein an aperture spaced from the leading edge of the card and in alignment with the switch 4880 in a line of travel of the card. Thus when the aperture is reached by the switch 4880, the switch will be released and the binary one signal will be removed from the reset side 4846 of the flip-flop unit. Thus, the punch clutch will discontinue advancing and the card will stop in position in the punch unit ready to be punched with the coded information either from the reader unit or manually by the typewriter unit itself.

As the card advances through the punch unit due to the action of switch 4866, the leading edge of the card will engage a second switch which, when depressed, has an armature 4882 which is adapted to be disengaged from a normally closed contact 4884 and urged into engagement with a normally open contact 4886. The normally open contact is connected to the positive source of supply through a conductor 4888 thereby charging a capacitor 4890 having one end thereof grounded. As was stated above, the card was fitted with an aperture which is in substantial alignment with the switch 4880, and when this aperture is positioned over the switch 4880 the armature will return to its normal position in contact with terminal 4884, thereby discharging the condenser through a resistor 4894. The voltage at the upper end of resistor 4894 will be impressed on the reset side 4846 of flip-flop unit 4842 through a diode 4896, thereby switching the flip-flop unit 4842 back to its normal state. When the flip-flop 4842 is switched to its normal state, a binary one output level appears at the output terminal of the set side 4844 thereby removing the punch clutch signal from terminal 4852 and deactivating the punch clutch. The card is now in position with relation to the punch unit to be encoded with information either from a reader unit or from the typewriter unit itself.

The circuit has also been provided with a manual card feed function wherein a switch 4898 is adapted to be moved from one position in contact with a grounded terminal 4900 to a second position in contact with a terminal 4902 connected to the 15-volt source of supply

through resistor 4874. When the switch is manually actuated to a position in contact with terminal 4902, a positive source of potential is impressed on the set side 4844 through an RC coupling circuit 4904 thereby switching the flip-flop 4842 to a condition where a binary zero level voltage appears at its output terminal on the set side. As in the above situation, this binary zero is inverted by gate 4850 and impressed on the punch clutch to advance the card through the punch unit. When the card is being advanced through the punch unit, it may be desired to 10 punch a delete code into the card, an output terminal 4906 is provided which is adapted to be attached to a delete code input terminal 4908 (FIGURE 28) through a diode 4910.

Thus as the card is being advanced through the punch unit, a delete code is continuously being generated and fed to the delete code output gate 2796 and thence through the delete code output terminal 2798. A system has been described wherein the card to be punched is accurately positioned within the punch unit, two cards being positioned in exactly the same position each time a card is fed, and also wherein a card may be passed through the punch unit manually while punching a delete code into the card. It is to be understood that the positions of the switches with respect to the card being fed therethrough are not critical and may be designed to be engaged by the card in any manner which will suitably actuate the control circuit, as described above.

FORMAT CONTROL SYSTEM

The format control system of the present invention relates generally to a system which is adapted to follow the rotary movements of the platen and the step-by-step movements across the platen of the typing mechanism. This vertical movement of the paper and horizontal movement of the mechanism across the paper evolves a coordinate system which may pinpoint any particular coordinate, either "Y" for the movement of the platen or "X" for the movement of the typing head. Thus, through the movement of the platen and the operation of its associated reader system, a series of independent signals may be emitted for each line. Also, a similar series of independent signals for each typing space, or step-by-step movement of the typing head, are emitted through the associated reader circuit. By coordinating pairs of signals from the "X" and "Y" reader units, control signals may be generated to control the operation of the writing system.

As was described in conjunction with FIGURES 1, 2 and 3, a vertical and horizontal reader unit are provided on the typewriter unit itself and mechanically interconnected with the platen of the typewriter, in the case of the vertical reader, and with the back and forth, step-by-step movement of the typing head, in the case of the horizontal reader. While the system is particularly described in conjunction with a rotary type of typing head, it is to be understood that the relative movement of the platen or other horizontal positioning mechanism utilized in conjunction with a particular typewriter unit may be correlated with the horizontal reader.

For example, the step-by-step back and forth movement of the typewriter platen may be correlated with the particular position of the type in the horizontal reader unit. Similarly, the vertical motion of the paper with respect to the typewriter unit may be correlated with the vertical reader means in the case of a typewriter which does not use a rotary platen. Thus, this latter reader would be interconnected with some other means such as, for example, if the platen were moved vertically with respect to the typewriter machine itself.

For a better understanding of the format control system, hereinafter to be referred to as the FCS system, reference is made to a representative sample of an invoice illustrated in FIGURE 43, and it is to be understood that the sample may be utilized in conjunction with the type-

writer and horizontal-vertical reader unit illustrated in FIGURES 1 to 3. In programming a system provided with a format control function, a piece of paper to be operated on by the typewriter machine is suitably ruled into a plurality of horizontally spaced lines which are coordinated with the horizontal position of a particular operation which is desired to be performed on the paper and similarly, a plurality of vertically spaced lines are drawn which are coordinated with the particular position of an operation which is desired to be performed, such as indexing and the like.

Referring particularly to a sample invoice 4919 illustrated in FIGURE 43, the upper portion, excluding the heading has been prepared for the user to generate horizontal and vertical tapes for use in the horizontal and vertical readers. It is seen that a plurality of punch off, reader on, vertical skip functions are desired to be performed as the typing head advances in step-by-step horizontal movement across the invoice. Also a plurality of line feed operations are desired in the vertical direction as the particular typing operation carries the typing head to the end of the sample invoice. While only the upper portion of the invoice has been programmed, it is to be understood that the entire invoice would be programmed to incorporate a coordinate for each typing space at which an operation is to be performed. The remainder of the horizontal spaces would appear in the area between the number one and seven positions indicated.

Accordingly, it is necessary to program a horizontal 30 tape which is correlated in position with the particular operations illustrated and also a vertical tape must be programmed which is correlated with the particular index operations which are desired. These horizontal and vertical tapes are adapted to be suitably positioned into the 35 horizontal and vertical readers described in conjunction with FIGURES 1 to 3, to correlate the movement of the typewriter platen and the typing head with a particular position or coordinate point on the paper being typed. Thus, when a coincidence of horizontal and vertical position 40 signals are received, a particular operation may be performed automatically by the format control system.

In order to control the operation of the system is described above, it is necessary that a coded vertical and horizontal reader tape be prepared by following through 45 the steps of typing the first invoice. Referring to the sample invoice in FIGURE 43, the horizontal reader unit will be first described. It is seen that the sample invoice has been ruled off by seven vertical lines numbered 1 through 50 7 and labeled "manual punch off," automatic punch on and reader on," "reader off, manual," "automatic-punch off-reader on," "tab," and "reader off, vertical skip." While these particular functions relate to the upper line below the "Ship to" address, it is to be understood that any function which is to be performed anywhere on the sheet 55 will have a corresponding vertical line with a number and the function to be performed without regard to the particular horizontal line containing the function.

The particular functions illustrated, such as punch off, punch on, will be programmed into the particular machine 60 function gates described in conjunction with FIGURE 25 and also it is to be understood that any of the machine characters or numerals may be programmed into the system such as, for example, the date or any other repetitive type of information. These particular characters will 65 be programmed into the typewriter input logic section illustrated in FIGURE 23, as will be hereinafter explained in conjunction with the format control output circuit. Thus, it is seen that the typewriter logic portion of the writing system is utilized for both the normal and format control 70 operations to alleviate the necessity of a duplication of circuit components.

In programming the horizontal tape, the sample invoice is inserted into the typewriter machine and a piece of tape is fed through the punch unit 81 mounted on the 75 right side of the typewriter 75. After the paper is posi-

tioned, the system is turned on and the numeral 1 is typed at the proper position indicated on the invoice and the corresponding code is punched in the tape. Then a plurality of spacing operations are performed until the number two position is reached corresponding to an automatic punch on and reader on situation. When this point is reached, the numeral two is typed and punched. The horizontal reader is then again spaced along until position number three is reached and a three is typed and punched, and so on down the line until a number seven is typed, which corresponds to a reader off, vertical skip or index. When the tape is removed from the punch unit, it will be noted that the tape appears exactly as a horizontal layout of the sample invoice, that is the number one will be punched, a plurality of spaces and then the number two, etc. This horizontal tape is adapted to be placed into the horizontal reader unit 116 to the upper right of the typewriter machine 75 and the tape will exactly follow the movement of the carriage mechanism due to the mechanical connection therebetween.

The vertical tape is produced in a manner similar to the production of the horizontal tape, wherein the sample invoice is positioned in the machine at the upper edge of the sheet. A succession of line feed are performed until a line on the paper is reached where a function is desired to be performed, the function corresponding to a function programmed into the horizontal reader tape. For example, all of the functions programmed into the horizontal reader tape described above would be at the number one position, indicated at the right edge of the figure, in the vertical tape and a line feed would be performed for number two and number three, and so forth. It is to be noted that each of the vertical ordinates are specifically numbered and a code is punched in the area where a particular function is to be performed. It is to be understood that a vertical code is punched in each line where a function or operation is to be performed, irrespective of where function or operation appears on the line. Thus, the entire sample invoice is programmed into a system of vertical ordinates and horizontal abscissas to evolve a coordinate system in which any particular point on the sample invoice paper may be designated by a pair of coordinates.

After the horizontal and vertical reader tapes have been produced, the horizontal tape is inserted into the horizontal reader unit 116 and the vertical tape is inserted into the vertical reader unit 114, and a sheet of paper, such as the sample invoice, programmed is inserted into the machine by rolling the platen in a conventional manner. As the typewriting machine goes through its normal functions in operating on the sample invoice, the vertical reader unit will exactly follow the movements of the platen and the horizontal reader will exactly follow the movements of the typing head, the latter indicating the position of the typing head irrespective of the position of the platen with respect to the typing head. Thus the horizontal reader tape will move back and forth in the reader in accordance with the back and forth movement of the typing head.

When the end of a line is reached and a carrier return operation is performed, the horizontal reader tape will return to its starting position to scan the next line again. A preferred embodiment of the horizontal and vertical readers are of the same general type so that described in conjunction with FIGURES 8 and 9, that is, a solar cell type of circuitry producing an output signal in accordance with the light directed through the apertures punched into the tape. These electrical signals are fed to the multiple channel reader units 114 and 116 and the electrical inputs thereof are fed to a plurality of input terminals 4920 to 4930 (FIGURE 44) corresponding to channels one to four and six and seven respectively, in the vertical section and input conductors 4932 to 4942 corresponding to channels one to four and six and seven in the horizontal reader unit.

Referring first to the vertical reader unit (FIGURE 44) it is seen that the inputs in channels one to seven are fed to the set sides 4948 to 4958 of a plurality of flip-flop units 4960 to 4970, respectively, through a plurality of RC coupling circuits 4972. The flip-flop units are reset by a conductor 4976 connected to the reset sides 4980 to 4990 through a plurality of RC coupling circuits 4492. The signal for the reset function is provided by a conductor 4994 connected to the output gate 2714 of the index pickup unit 2712 (FIGURE 26). Thus, the vertical section is reset each time an indexing operation is performed, whether the indexing is a part of a carriage return function or purely the result of an index. The outputs of flip-flops 4960 to 4966 are connected to a plurality of norgates 5000 to 5020 by means of a plurality of conductors 5022 and necessary emitter followers 5024 have been provided where a large number of gates are being supplied and a large current level is required.

20 The output signals from the set sides of the channels six and seven, flip-flops 4968, 4970 are supplied to a pair of norgates 5028 and 5030 and the signal from the reset sides 4988, 4990 are fed to a plurality of gates 5032 and 5034. It is to be noted that the gate 5028 corresponds to a reading six and seven and the gate 5032 corresponds to a reading of not six and not seven. The not six and not seven signals are fed through an emitter follower circuit 5038, due to the fact that a large number of gates is being supplied from this output. As in the case of the 30 norgates described above a plurality of binary zeros at the inputs thereof will produce a binary one at the output terminal, and the outputs of gates 5000 to 5018 are fed to a plurality of inverter gates 5040 to 5058. The binary zero output thereof, when a particular gate has 35 been actuated, is fed to a plurality of output terminals 5060, the terminals corresponding to a reading in the particular channels as indicated.

A strobing signal has been provided by means of a conductor 5064, which is fed into the inputs of gates 40 5032 and 5028. Accordingly, the output of gates 5032 will remain at a binary zero level until such time as the strobe signal is impressed on conductor 5064, thereby lowering the input to these gates to a binary zero level. When the strobe signal is impressed on the gates, a 45 binary one signal will be received at the output terminal, this signal being inverted to a binary zero and fed to the respective gates 5000 to 5020. It is to be noted that the output of gate 5034 controls the strobing of gates 5000 to 5016, and the output of gate 5030 controls the 50 strobing of gates 5018 and 5020. In this manner, the inputs to the gates 5000 to 5020 can be at a maximum of five including the strobe input due to the fact that the input for the strobe signal is fed to gates 5032 and 5028, which are in turn connected to the inputs of gates 5000 to 5020.

It is to be noted that the gate 5020 corresponds to a letter "H," as indicated to the right of the drawing, and the output on this conductor 5068 is utilized to home the vertical reader unit to a start position, as will be more 60 specifically explained hereinafter. Thus the output signals corresponding to a particular combination of the input signals from the vertical reader unit have been impressed on a plurality of output terminals 5060. Referring now to the horizontal reader unit 5070 illustrated partially at the lower half of FIGURE 44 and FIGURE 45, it is seen that the inputs from channels one through four and six and seven are fed to the plurality of input conductors 4932 to 4942, respectively. The signals impressed on these latter conductors are fed to the 65 set sides 5072 to 5082 of a plurality of flip-flop units 5084 to 5094, respectively, through RC coupling circuits 5096.

Like the vertical flip-flop units, the set sides 5072 to 5082 are normally at a binary one level at their output 70 terminals and the reset sides 5098 to 5108 are at a binary

zero at their output terminals. A reset signal is provided to the reset sides 5098 to 5108 by means of a conductor 5112 and a plurality of RC coupling circuits 5114 connected thereto. Emitter follower circuit 5116 (FIGURE 45) is provided to boost the current level of the signal being fed to reset these latter flip-flop units. The outputs from the set and reset sides of the flip-flop units 5084 to 5090 are fed to a plurality of output norgates 5122 to 5170 by means of a plurality of emitter followers 5172 and conductors 5174. The outputs of the channels six and seven flip-flop units 5092, 5094, are fed to a plurality of three norgates 5178, 5180 and 5182 wherein the gate 5178 corresponds to a reading in channel six and channel seven, gate 5180 corresponds to a reading in channel seven only and gate 5182 corresponds to a reading in neither channel six nor channel seven. The outputs of the gates 5178 to 5182 are fed to a plurality of inverter gates 5184 to 5188 which inverts the signal and feeds it to the output gates 5122 to 5170 through emitter followers 5192 and conductors 5174.

It is to be noted that the strobe signal is provided by a conductor 5190 to the output gates 5178 to 5182 in a manner similar to that described in conjunction with channels six and seven of the vertical reader unit. The outputs of norgates 5122 to 5170 are fed to a plurality of output terminals 5198 corresponding to the respective numbers and letters indicated at the right edge of the figure through a plurality of inverter gates 5200 to 5248. The strobe signal impressed on conductors 5064 for the vertical channels six and seven and conductor 5190 for the horizontal channels six and seven is impressed on conductor 5250 from the reader control circuit strobe signal in FIGURE 26, and is passed through a conductor 5252 and an emitter follower 5254 to the respective strobing conductors 5064 and 5190.

The strobe signal for the vertical and horizontal reader units is generated by a single shot multivibrator 5256 receiving its input from the strobe channel output which is not being used for an information channel. In practice it has been found that one of the information channels or the sprocket channel may be used for this purpose. The input to single shot multivibrator 5256 is fed from the output terminal of the horizontal reader stroke channel circuit 5258 by means of a conductor 5260 and an RC coupling circuit 5271. The pulsing strobe signal from the strobe channel is impressed on the input circuit, including an RC coupling circuit 5255, to a single shot multivibrator 5257. The output of the multivibrators 5257 is fed to one of two input conductors 5259 of a gate 5261. A second input conductor 5265 is provided to the gate 5261 to inhibit the function thereof during the tab function.

During the tab and carriage return functions, the horizontal reader tape is being passed through the reader due to the mechanical connection to the carriage mechanism. Accordingly, it is desirable to inhibit the strobe signal to the horizontal and vertical readers during these functions and to this end the conductor 5265 is connected to the tab pickup conductor 2694 (FIGURE 26) through a conductor 5267. Due to the fact that the pulse from the strobe channel will have disappeared prior to the completion of the tab function, a simulated strobe channel pulse is generated by the end of the tab pulses. The falling edge of the pulse is fed through the conductor 5267 and a conductor 5269 to single shot multivibrator 5256 by means of a negative RC coupling circuit 5273. Thus a strobe pulse will be generated at the end of the tab function by the multivibrator 5256. Similarly, a conductor 6001 is connected to the output circuit of the end of index pickup, a function performed as a part of the carriage return, to generate a pulse. This pulse is fed to the multivibrator 5256 by means of conductor 6001 and an RC coupling circuit 6003. This strobe shot strobos the information stored in the vertical reader to the vertical flip-flops.

The inhibit signal for gate 5261 during the carriage return function is generated by a flip-flop 5273 which is nor-

mally at a condition wherein the set side 5275 is at a binary one and the reset side 5277 at a binary zero. The output of the reset side 5277 is fed to the input conductor 5265 by means of a conductor 5279 and a diode 5281. Thus, the inhibit signal is not present on conductor 5279 during the period when the carriage return function is not being performed. The input from the carriage return pickup coil is impressed on the set side 5275 of flip-flop 5273 by means of a conductor 5283 and an RC coupling circuit 5285. At such time as the reader input carriage function is being utilized, the carriage return signal is received from the carriage return circuit in FIGURE 25 by means of a conductor 5287 and diode 5289 and when the reader is not being utilized, as in a manual input situation, the carriage return signal is received from the carriage return output hub 2952 of the punch logic of FIGURE 28 by means of a terminal 5291 and a diode 5293. When a signal is received at flip flop 5273 from either conductor 5287 or terminal 5291, the flip flop is switched to its set condition wherein a binary one signal is impressed on conductor 5279 to inhibit gate 5261.

At the end of the carriage return function, a signal is received from the end of carriage return pickup coil and fed to the reset side 5277 of flip-flop 5273 by means of a conductor 5293 and RC coupling circuit 5295. In this way the inhibit is removed from gate 5261 by the resetting action. Insofar as an index operation is associated with each carriage return function and occurs first, it is necessary to inhibit the index end of function signal from being fed to gate 2674 to recycling of the control loop 2414. This inhibit is required due to the fact that the end of the index function will generate a strobe signal for the format control system input logic, an undesirable occurrence. Accordingly, the inhibit signal from the flip-flop unit 5273 is also fed to an input conductor 5297 to end of index gate 2715 which inhibits the operation of this gate and precludes the recycling of the control loop from the index function. The recycling pulse for the control loop 2414 is supplied by the end of a carriage return pickup coil to strobe the FCS input logic. The initial conditions of the flip-flop 5273 are set by the grounding circuit found in FIGURE 26 through the conductor 4326 and an RC coupling circuit 5299. The output of the single shot multivibrator 5256 is fed by means of a conductor 5264 to a gate 5265 which is connected to the horizontal reader strobe section by means of a conductor 5267, to strobe the information received in the reader unit from the punch tape through to the horizontal flip-flop units described above. It will be noted that the single shot multivibrator 5265 provides a time delay between the reading of the strobe channel signal and the strobing of the information contained in the tapes to allow the information to be passed from the gates 5000 to 5020 and 5122 to 5170 for the previous input to the output terminals prior to strobing the readers to input information to the flip-flop units for the subsequent input.

From the foregoing, it is seen that the horizontal reader unit is strobed with each step-by-step motion of the typing head while the vertical reader is strobed once for each line. This is true due to the fact that the information for each line is the same in the vertical direction, thus requiring only one set of vertical codes for each line.

Referring now to FIGURE 46, there is illustrated a plurality of negative "and" gates or "nand" gates 5300 which have a first set of input terminals 5302, one for each of the gates 5300, which correspond to the "Y" or vertical reader unit output and a plurality of second input terminals 5304 which correspond to the "X" or horizontal reader unit outputs. These terminals 5302 and 5304 are suitably connected to the output terminals 5060 and 5198 respectively, to provide an output at a plurality of respective output terminals 5306 corresponding to each of the gates 5300. It is to be noted that a coincidence of a signal received on both the vertical and horizontal reader unit output terminals is the determining factor which provides an

output at terminals 5306. Thus a plurality of gates 5300 are provided for the various combinations of "X" and "Y" coordinates and the largest number of combinations of coordinates at which a function is performed will determine the number of "nand" gates to be provided.

Referring to FIGURE 47, the outputs of the coordinate "nand" gates 5300 are fed to a program emitter matrix 5310 which generally comprises a counter means 5312 in the form of a plurality of diode steering network flip-flop units which feed the outputs thereof to a plurality of norgates 5314. The outputs of norgates 5314 are fed to an outputting matrix 5316 which is "enabled" to output signals therefrom by means of a plurality of enabling means 5318 taking the form of flip-flop units.

Specifically, the outputs of the coordinate "nand" gates 5300 are fed to a plurality of input terminals 5320, 5322, 5324 which supply these input signals to the set sides 5326, 5328 and 5330 of a plurality of flip-flop units 5332, 5334 and 5336. The flip-flop units 5332, 5334 and 5336 are normally at a binary one level at the output terminals of the set sides 5326, 5328 and 5330, and a binary zero at the output terminals of the reset sides 5340, 5342 and 5344. These input signals are fed through a plurality of RC coupling circuits 5346, 5348 and 5350 and the outputs of the reset sides are supplied to a plurality of output conductors 5352, 5354 and 5356.

Referring now to the matrix circuit 5316, it is seen that the output from the reset side of the flip-flops 5332, 5334, 5336 are fed to the cathodes of a plurality of diodes 5364 to 5378 and the outputs of the various norgates 5314 are fed to each respective anode of the diodes 5364 to 5378 by means of a plurality of emitter follower circuits 5380 to 5394, corresponding to each horizontal line of diode circuits, through a plurality of resistors 5396 to 5410. The output of any particular resistor-diode combination in any one line is provided from a plurality of output terminals 5414 to 5428 and any particular line is controlled by the particular signal on emitter follower unit 5380 to 5394. It is seen that if a binary one level signal is being fed from a particular emitter follower circuit, as for example, emitter follower 5380 to the first resistor-diode combination 5396, 5364 and a binary zero output signal level is appearing on the reset side of flip-flop unit 5332, the signal will merely pass through the resistor 5396, the diode 5364 and down to the flip-flop unit 5332. Thus, the signal will not be outputted from output terminal 5414.

However, if an input signal is received on input terminals 5320 to switch the condition of flip-flop unit 5332, thereby putting a binary one output signal on the reset side of flip-flop 5332, the diode 5364 will be back biased due to the signal from the reset side 5340 and the drop across resistor 5396. This is true because a larger positive voltage will appear at the conductor 5352 than will appear at output terminal 5414 thereby back-biasing the diode 5364 and permitting the signal to be outputted from terminal 5414. Thus, by pulsing a particular flip-flop unit, thereby choosing a vertical section of the diode matrix, and by energizing a particular portion of the counter 5312, a particular horizontal line will be chosen, an output terminal will be chosen to output a control signal. It is to be understood that while each portion of the matrix is illustrated as being a diode-resistor combination and an output terminal, that any number of these combinations may be chosen to be controlled by a particular combination of an output gate 5314 and flip-flop unit 5318.

The particular horizontal line of output hubs 5414 to 5428 are chosen in sequential order by the operation of the counting means 5312. The counting means 5312 generally comprises a plurality of sequentially interconnected diode steering flip-flop units 5434 to 5440 which are interconnected in such a manner as to sequentially energize each of a plurality of gates 5442 to 5456. The first diode steering network flip-flop 5434 receives a signal from a

norgate 5460 which has a plurality of inputs, the first of which is from an emitter program inhibit conductor 5462 which receives a signal from FIGURE 49, as will be hereinafter explained, through an emitter follower 5464. A second input to gate 5460 is provided from a gate 5468 and conductor 5470 which corresponds to a gate sensing the conditions of each one of the flip-flop units 5332, 5334 and 5336.

It will be noted that each one of the inputs to the gate 5464 is provided from the reset sides 5340, 5342 and 5344 of the flip-flop units and it is necessary that at least one of these flip-flop units have been switched to its enabling condition to provide a binary one input signal to the gate 5468. With this binary one input, the output of the gate will be at a binary zero level and this binary zero will be fed to the input of gate 5460, thereby removing the inhibit function from the gate in the situation where none of the flip-flop units 5332 to 5336 have been switched. It is to be understood that, while only three flip-flop units have been illustrated, a large number may be provided in accordance with the number of automatic functions to be performed by the system.

It is seen that when the inhibit signal is provided from conductor 5462, the program emitter inhibit function, this signal is also fed to a conductor 5474 to a plurality of grounding circuits 5476, 5478 and 5480, which are connected to the outputs of each of the RC coupling circuits 5346, 5348, 5350, thereby grounding these outputs. Thus, when the inhibit function is provided on conductor 5462, the inputs to the set sides 5326, 5328 and 5330 of the flip-flop units are grounded thereby precluding the enabling of any of these flip-flop units.

The main signal pulse is fed to gate 5460 by means of a conductor 5492 which receives an input from the pickup in the reader section. This input signal will switch the flip-flop unit 5434 from a binary zero at its reset side 5494 and a binary one at its set side 5496 to the reverse situation where a binary one appears at its reset side 5494. The output of the reset side 5495 is fed to gates 5444, 5448, 5452 and 5456 and the output of the set side 5496 is fed to gates 5442, 5446, 5450 and 5454 by means of a plurality of conductors 5500. Also, the output of the set side 5494 of flip-flop 5434 is fed to the input of flip-flop 5436 by means of a conductor 5502. However, it is not until the flip-flop unit 5434 has switched back to its binary zero state at the reset side that the flip-flop unit 5434 will be switched. Accordingly, the reset side 5504 is fed to the gates 5442, 5448, 5450, 5452 and 5456 and the output of the set side 5406 is fed to gates 5444, 5452 and 5454. Also, the output of the set side 5504 is fed by means of a conductor 5508 to the input of flip-flop 5438.

However, as in the above situation, the flip-flop unit 5438 is not switched to its opposite state until such time as the flip-flop unit 5436 is switched back to its original state and, accordingly, it is only after the fourth pulse that the flip-flop 5438 is switched. As in the above case, the output of the reset side of flip-flop 5438 is fed by means of a conductor 5510 to the input of flip-flop units 5440 to switch it back and forth. In this situation, the flip-flop unit 5440 is switched every eighth input pulse from gate 5460, or at such time as flip-flop 5438 is switched back to the normal state. The output of flip-flop units 5438 and 5440 are supplied to the gates 5442 to 5456, as indicated by the interconnections through conductors 5500. If the operation of each of the flip-flop units 5434, 5436, 5438 and 5440 were followed through to the eighth pulse, it will be seen that, if the counter is desired to be reset after each eighth pulse, it is necessary only to reset the flip-flop 5440 because the rest of the flip-flop units 5434, 5436 and 5438 will be in their original state of a binary zero output level at the reset sides of each. Accordingly, the output of gate 5456 is provided through a conductor 5514 and a negative RC coupling circuit 5516 to the reset side of

flip-flop 5440 to reset the flip-flop unit. In this manner the counter 5312 is ready for a sequential operation of another eight pulses.

The outputs of the norgates 5442 to 5456 are provided with a strobe signal from a conductor 5520 which is connected to the main input strobe signal from terminal 5250. Thus each time a strobing signal is impressed on input terminal 5250, the information stored in gates 5442 to 5456 are strobed to the matrix 5316 and outputted therefrom if the proper flip-flop units 5332 to 5336 have been switched. An emitter follower circuit 5522 has been provided in the strobing circuit due to the large number of gates which are controlled from a single strobing signal.

The diode steering flip-flops 5434 to 5440 are reset after each sequence of operation by means of a zero program emitter circuit comprising generally an input gate 5530, which has a plurality of input terminals 5532 from any suitable source and a fourth input terminal 5534 from the grounding circuit in the reader section. This latter conductor 5534 is connected to conductor 4326 in FIGURE 26 to provide a pulse on initial turn-on to initially set the conditions of the diode steering flip-flops 5434 to 5440. The input terminals 5532 provide a signal which is adapted to set the flip-flop units from a signal source, as for example the outputs of the "nand" gates 5300 or from an output terminal in the diode matrix circuit 5316, and the binary zero output of norgate 5530 is fed through an RC coupling circuit 5538.

The positive output signal from RC coupling circuit 5538 is fed to the flip-flops 5434 to 5440 by means of a single shot multivibrator 5540, a pair of emitter followers 5541, 5542, a conductor 5544 and a plurality of RC coupling circuits 5546 connected to each of the reset sides of the diode steering flip-flops. This set signal is also fed to flip-flops 5332 to 5336 by means of a diode 5548, emitter follower 5550 and a conductor 5552. The conductor 5552 is connected to the reset side 5340 to 5344 through a plurality of RC coupling circuits 5554. Thus, the flip-flops 5332 to 5336 and 5434 to 5440 are reset by the trailing edge of the resetting pulse.

The output terminals of 5414 to 5428 of the matrix circuit 5316 may be interconnected in any suitable fashion to provide a sequential stepping to the various levels of the diode matrix as, for example, from the output terminal 5414 controlled by flip-flop 5332 to the output terminal 5416 controlled by the same flip-flop 5332, etc., down the vertical line of the matrix. Thus a sequential operation of the matrix may be provided by a single input to the flip-flop unit 5332 and a plurality of pulses to the diode steering flip-flop 5434. At any point of the operation or after a single operation, the output signal from any of the terminals may be fed to either the gate 5530, in which event the entire flip-flop section 5318 and counter section 5312 will be reset to end the count, or to a plurality of stop input terminals 5560 which supply a signal to a stop gate 5562. This gate is provided in order to reset each of the flip-flop units 5332 to 5336 in the event it is desired to stop the counter at some intermediate count, for example count four, and start at the next count, for example count five. The operation of the format control system will be stopped temporarily pending the receipt of additional signals into the flip-flop section 5318 to continue the count.

The output of gate 5562 is inverted by gate 5564 and fed to the emitter follower circuit 5550 and the reset sides 5340, 5344 through a diode 5566. The diode 5548 is then back-biased to block a resetting signal to the diode steering flip-flop section 5312. Accordingly, each time a stop signal is received at the gate 5562, either from the matrix 5316 or from the output terminals 5306 of the "nand" gates, a pulse is fed through conductor 5552 to the flip-flop units 5332 to 5336 to reset these flip-flop units. As was described above, when the flip-

flop units are reset, a signal will be passed from gate 5468 to the input terminal of gate 5460 thereby inhibiting any further signals from being passed into the diode steering flip-flop units. A base emitter current limit resistor 5568 is connected to ground to provide a current path for the excess current of the resetting circuits.

In certain situations, as for example when the diode matrix is being operated by switching from one vertical line of output terminals to another vertical line, it is necessary to delay the strobe signal to the norgates 5314 thus insuring that the flip-flops 5312 have been pulsed to the desired count. In this situation, a signal is fed to the stop gate 5562 which resets the flip-flops 5318. When the flip-flops 5318 are reset, an inhibit signal is provided at the input terminal to gate 5460 from gate 5468. The next input signal to flip-flop section 5318 removes this inhibit signal and the falling edge of the output pulse from gate 5460 pulses the counter to the next step. In order to insure that the counter has been stepped before the strobe pulse is fed to gates 5314, a delay strobe pulse is generated in single shot multivibrator circuit 5580, this delay pulse being superimposed on the strobe pulse from emitter follower 5522.

The effect is for the strobe pulse from conductor 5520 to drop to a binary zero level while a binary one pulse is fed from the delay strobe circuit 5580. The delay pulse drops to a binary zero level prior to the main strobe pulse rising to a binary one level, thereby providing a period of time in which both pulses are at the binary zero level. It is to be noted that this binary zero level occurs late in the period of the main strobe pulse to delay its effect. The delay strobe circuit generally comprises a single shot multivibrator 5582 which receives an input signal from the output of multivibrator 2420 in FIGURE 35 by means of a conductor 5584 and RC coupling circuit 5586. The output of the multivibrator 5582 is fed through a gate 5588, an emitter follower 5590 and a diode 5592 to the conductor connected to the output terminal of the emitter follower 5522. Thus, the two strobe signals are superimposed one on the other, to provide a delayed strobe to the gates 5314.

Referring now to FIGURES 48 and 49, there is illustrated a plurality of machine function and commonly used character norgates which are adapted to receive the signals from the output terminals 5414 to 5428 of the diode matrix 5316 or nand gate 5300 outputs. While all of the machine functions and certain of the commonly used characters have been provided special gates, it is to be understood that certain of the output hubs from the program emitter diode matrix will be fed to the digital output switches, as illustrated in FIGURE 50 and to be hereinafter explained. Also, as described above, it is to be understood that a sequence of machine functions or character printing functions may be performed by cascading the output of one output terminal in the diode matrix section to another output terminal, the sequence of horizontal lines being activated by the counter. In this manner, the terminals to the machine function gates or the digital switch illustrated in FIGURE 50 are connected in sequential operation in accordance with the energization of the horizontal rows of output terminals of the diode matrix.

Referring now to the nonprint portion of FIGURE 48, a nonprint gate 5600 is provided having a plurality of input terminals 5602 which are adapted to be connected to the nand gate output terminals 5306. The output from gate 5600 is fed through an inverter gate 5604 and a diode 5606 to an output conductor 5608 which is connected to the nonprint flip-flop unit in the machine function control circuit by means of an input terminal 5608 (FIGURE 25). The output of gate 5604 is also fed by means of a conductor 5618, a diode 5620 and a conductor 5622 to a reader clutch inhibit flip-flop 5624. The flip-flop unit 5624 includes a set side 5626 which is normally at a binary one voltage level at its output terminal

and a reset side 5628 which is normally at a binary zero level at its output terminal. The signal from the nonprint gate 5600 provides a switching signal through an RC coupling circuit 5630, the trailing edge of which switches the conditions at the flip-flop 5624 to impress a binary zero signal on the output conductor 5632 connected to the reader control circuit in FIGURE 26.

This signal is fed through a grounding circuit 5634 (FIGURE 26), the output of which is connected to the output conductor of the reader clutch gate 2476 by means of a conductor 5636 and the conductor 2767. Thus the circuit 5634 acts as a grounding circuit for the output pulse from gate 2476 when a binary one signal is impressed on conductor 5632 to preclude the advancing of the reader clutch.

When a signal is received at the FCS nonprint gate, the flip-flop unit 5624 is switched to the opposite condition wherein the set side 5626 is at a binary zero level output and the reset side 5628 is at a binary one level. Thus the signal to the reader clutch output conductor through the gate 5634 is removed and the output pulses to the reader clutch are provided. Similarly, a reader-on gate 5660 having a plurality of input terminals 5662 is provided and the output thereof is fed to the set side 5626 of flip flop unit 5624 through an inverter gate 5663, a conductor 5664, a diode 5666 and the conductor 5622. The operation of the "reader-on" circuit is identical in function to the nonprint mode with respect to the flip-flop unit 5624. The outputs of both the nonprint gate 5600 and reader-on gate 5660 are fed to the node 2416 in FIGURE 26 by means of an output conductor 5668 and an RC coupling circuit 5670. In this way a cycling pulse is fed to the control loop 2416 during this operation of the FCS portion of the writing system.

The punch-on function for the format control system is provided by a punch-on gate 5676 having a plurality of inputs 5678 which are adapted to be connected to the output nand gates as in the above situation. The output of gate 5676 is fed to the punch-off flip-flop unit in FIGURE 25 by means of a pair of gates 5686, 5688 and a diode 5690. A punch-off norgate 5698 is provided having a plurality of input terminals 5700 which are connected to the output terminals of the "nand" gates. The output signal from gate 5698 is fed through an inverter gate 5702 and a diode 5704 to the punch-off flip-flop in FIGURE 25. When a binary one signal is received at input terminal 5700, a binary zero output will be fed into the input terminal of gate 5702, the output of which is fed to the punch-off circuit.

The reader-stop function is provided by a reader stop input gate 5710 which is provided with an input signal from a plurality of input terminals 5712. The output of the gate 5710 is fed to the reset side 5628 of the flip-flop 5624 through a gate 5714 and an RC coupling circuit 5716. Thus, the operation of the reader unit is prohibited by the grounding of the reader clutch signals through the conduction of current in the collector emitter circuit of the transistor contained in gate 5634. The output of gate 5714 is also fed to a reader stop flip-flop 5717 (FIGURE 45) by means of a conductor 5719, to be hereinafter explained.

A plurality of commonly used character imprinting gates are provided, such as the characters "R", "C", ":", "/", "*" and "-", and as many of these characters may be provided as required. Specifically, the letter R is provided by means of a gate 5720 having a plurality of input terminals 5722 connected to the output of the "nand" gates. The output of the gate 5720 is connected to the output conductor 5724 through a gate 5726. This output conductor 5724 is connected to the input terminal of the typewriter input logic section which produces the latter R at the typewriter unit. This connection will depend on the particular code being utilized with the typewriter unit. Similarly, the letter C is provided through an input gate 5730 from a plurality of input terminals 5732. The

output of gate 5730 is connected to an output conductor 5734 through a gate 5736. As in the situation with the letter R, this letter is also connected to the typewriter input logic section at the proper terminal to produce the letter C at the typewriter unit.

As stated above, the format control system is provided with a feature wherein the format control circuitry may be actuated to a starting or home position in order that the user may correlate the paper with the position of the horizontal and vertical tapes in both horizontal and vertical reader units. To this end a homing circuit 5750 has been provided which, when actuated, will return the carriage to the start or initial position and continuously index the platen until such time as a home signal is received from the vertical reader unit. This home signal has been incorporated in the letter H described in conjunction with the vertical reader unit.

Referring now to the home circuit 5750, a program home switch circuit 5752 is actuated to the home position wherein armature or blade 5754 is placed into contact with a normally open terminal 5756 to charge up a capacitor 5758 from a 15-volt source of power supply through a resistor 5760. On release of the switch 5752, the capacitor 5758 is discharged through a diode 5764 and resistor 5766 to provide an input pulse to the set side 5768 of a program home flip-flop unit 5770. A signal from the program home flip-flop 5770 must be introduced by means of the conductor 4143 to the reader control circuit to initially provide the reader logic strobe to start the program home operation. The output of the set side 5768 is fed to a gate 5772 having a plurality of input terminals which are assumed, for purposes of discussion, to be at a binary zero level. The output of gate 5772, a binary one, is fed through a diode 5776 and a conductor 5778 to a carriage return output conductor 5780. The carriage return output conductor 5780 is connected to a carriage return input terminal 5782 (FIGURE 25), which actuates the carriage return output coil 2000.

Inasmuch as an index operation is associated with a carriage return function, and end of index signal is generated in the index coil 2712 (FIGURE 26) which is fed to an input conductor 5784 by means of a conductor 5786 and output terminal 5788. This end of index signal is fed to the set side 5790 of a flip-flop unit 5792 through an RC coupling circuit 5793 to switch the flip-flop unit from a binary one output level at the output terminal of the set side 5790 to a binary zero output level. This binary zero is fed to one of the input conductors of a gate 5794 by means of a conductor 5796. The signal from gate 5772 is also fed to the set side 5800 of a flip-flop unit 5802 by means of an RC coupling circuit 5804. This signal provides a binary zero output at an output conductor 5806.

As stated above, a conductor 5250 is connected to the reader logic strobe output conductor 1454 (FIGURE 26) to provide an input signal to the flip-flop unit 5792. After the index pickup signal has been generated, a reader logic strobe signal will be impressed on conductor 5250 and this signal will be impressed on the input to gate 5794 by means of a conductor 5812. This strobe signal is normally at the binary one level and drops to a binary zero level for a short period of time. It is also seen that this strobe signal is fed to the input to gate 5772 by means of a conductor 5814 and the signal level on this conductor will drop to a binary zero level in order to permit the output signal from flip-flop 5770 to initially pass through gate 5772. The trailing edge of the strobe signal is fed to the reset side 5816 of flip-flop units 5792 by means of RC coupling circuit 5818. This signal resets the flip-flop unit 5792 to provide a binary zero at the output of reset side 5816 and a binary one at the output of set side 5790, thus inhibiting the operation of the gate 5794.

However, prior to this inhibiting action, the binary zero level signal being fed to the gate 5794 through the conductor 5812 permits the gate 5794 to pass an output

signal to an index output conductor 5820 through a diode 5822. This index signal is connected to an index input terminal 5826 (FIGURE 25) to actuate the index coil 2018. The "end of index" pickup unit will generate a completed function signal and impress this signal on input terminal 5784 to reset flip-flop unit 5792 and provide a binary zero output signal on conductor 5796. When the strobe signal drops to a binary zero level, thereby dropping the signal level on conductor 5812 to a binary zero level, the gate 5794 will again provide an index signal to index the platen of the typewriter unit.

This indexing of the platen of the typewriter unit will continue inasmuch as an index pickup signal and a reader logic strobe signal are continuously generated. However, when the vertical reader unit reads the code for the letter "H" a home signal is generated in accordance therewith, which acts to inhibit the indexing operation of the flip-flop 5792. This home signal is impressed, through the conductor 5068, on the reset side of flip-flop unit 5802 by means of a diode 5832 and RC coupling circuit 5834. This signal reset flip-flop 5802 to provide a binary one signal at the output terminal of the set side 5800, thereby placing a binary one on input conductor 5806 to gate 5794. Thus the output of gate 5794 is inhibited in spite of the continual switching of flip-flop 5792 and the indexing operation of the machine is discontinued.

The input signal from the letter H conductor 5830 is also fed to the reset side 5838 of flip-flop unit 5770 by means of an RC coupling circuit 5840, and the input to gate 5772 is also inhibited by the binary one output signal at the set side 5868. It is to be noted that the switching back and forth of the flip-flop 5792 provides an alternate binary zero and binary one level signal into gate 5772 by means of a conductor 5842. However, this signal is not in phase with the signal from conductor 5814 inasmuch as the flip-flop unit 5792 is reset at the trailing edge of the stroke signal on conductor 5814. These two conductors are utilized to set the condition of gate 5772 to initially provide a carriage return signal to output conductor 5780. The initial conditions of flip-flops 5770 and 5802 are provided by RC coupling circuits 5844 and conductors 5846 connected to conductor 4326 in FIGURES 26. This conductor provides a grounding signal on initial power turn-on to set the initial conditions of the flip-flop units. It is to be noted that the conductor 5850 is connected to an inhibit conductor 5852 which provides an inhibit feature for the output gates for the various functions described above as for example, gate 5604 in the nonprint mode. The inhibit signal is generated in a portion of the circuit to be hereinafter explained.

The carriage return function is also provided by a carriage return gate 5856 having a plurality of input conductors 5858 connected to any one or a number of outputs of the nand gates 5300. The output of gate 5856 is provided to the carriage return output 5780 by means of a gate 5860 and a diode 5862. Similarly, an index function is provided by an index gate 5866 having input terminals 5868. The output of the gate 5866 is provided to the index output conductor 5820 through a gate 5870 and a diode 5872.

A similar operation to the home operation is performed by the vertical skip start gate 5880 and a vertical stop gate 5882 which are adapted to be connected to the flip-flop units 5802. The vertical skip start is provided with a plurality of input terminals 5884 which are adapted to receive an output signal from the nand gates 5300. The output of gate 5880 is fed through a gate 5886 and a diode 5888 to the conductor 5778 thereby impressing an output signal on the carriage return output conductor 5780. The signal from gate 5886 is also impressed on the set side 5800 of flip-flop unit 5802 in a manner similar to that described in conjunction with the homing circuit.

As in the situation with the homing circuit, the carriage return produces an end of index pulse which sets the conditions in flip-flops 5792, and accordingly places a bi-

nary zero on conductor 5796. When the reader logic strobe pulse is received on conductor 5250 it is impressed on the input to gate 5794 thereby producing an index pulse on output conductor 5820. This operation will continue until such time as a vertical stop signal is received on a plurality of vertical stop input terminals 5890. The output of vertical stop gate 5882 is fed to the reset side of the flip-flop unit 5802 by means of a gate 5842 and a diode 5894. With the resetting of flip-flop unit 5802, an inhibit is placed on the input terminal to gate 5794 thereby inhibiting the indexing operation of the gate 5794.

Referring now to FIGURE 49, there is provided a format control system on-off switch circuit 5900 which is adapted to switch the conditions of an on-off flip flop unit 5902 and thus control the operation of the format control system. Referring first to the system-on switch 5904, a capacitor 5906 is charged from a positive 15-volt power supply through a resistor 5908 and a switch blade 5910 which is adapted to be moved to a normally open terminal 5912. On release of the switch 5904, the blade 5910 returns to its normally closed position in contact with a terminal 5916 and the capacitor is discharged through a discharge resistor 5918 to provide an input pulse to the set side 5920 of flip-flop 5902 through an RC coupling circuit 5922. Thus the set side is provided with a binary zero output signal at the output terminal thereof.

When it is desired to turn the format control system off, an off-switch 5926 is moved into contact with a normally open terminal 5928 which connects the 15-volt power supply across a resistor 5930. Thus a positive pulse is fed to the reset side 5932 of the flip-flop unit 5902, thereby switching its conditions to the state wherein a binary zero appears at the output terminal of the reset side 5932 and a binary one appears at the output terminal of the set side 5920. The binary one output from the set side 5920 is fed to the set side 5626 of flip-flop unit 5624 by means of a diode 5940 and a conductor 5942 to switch the flip-flop to the condition wherein a binary zero appears at the set side 5626. Thus the inhibit from the reader clutch is removed and the reader section may operate normally.

However, when the "on" switch 5904 has been actuated and flip-flop 5902 has been switched to provide a binary zero at the output of set side 5920, the reset side 5932 will be switched to a binary one level output signal, the signal being fed through a conductor 5946 and an RC coupling circuit 5948 to the reset side 5628 of the flip-flop units 5624. Thus the flip-flop unit is switched to put a binary one level signal at the output terminal 5632, and the reader clutch is inhibited until such time as a signal is received from the nonprint or reader-on input gates 5600, 5660, respectively. This binary one signal from the reset side 5932 is also fed to the start flip flop unit in the reader section by means of a diode 5950 and an output conductor 5952 to provide a pulse to the start flip flop unit 2400 in FIGURE 26 thereby setting the desired conditions in the start-stop flip-flop 2400 (FIGURE 26).

The set side 5920 also provides an inhibit function for all of the function gates described above in addition to those to be hereinafter described through diode 5940 and the conductor 5942 and also an emitter follower circuit 5960 and a conductor 5962. Thus, it is necessary that the format control system switch 5900 be turned to the "on" position in order to operate the various function gates.

An initial, condition-setting circuit 5978 is connected to conductor 4326 (FIGURE 26), which provides a grounding signal to initially set the conditions of all the flip-flop units in this portion of the control system. A signal impressed on conductor 4326 provides an output signal from a gate 5978 which is fed to the reset side of a flip-flop unit 5980 and the flip-flop unit 5902 through an RC coupling circuit 5982 and a conductor 5984, respectively. Thus the initial conditions of the flip-flop units are set during the turn on of the main power. Additionally, a second resetting gate 5986 is provided and connected to

flip-flop unit 5624 by means of a conductor 5988 to set the initial condition of the reader clutch inhibit flip-flop.

The control of the program emitter portion of the format control system is provided by a program emitter inhibit circuit 6000 which includes the flip-flop unit 5980. The normal conditions of flip-flop unit 5980 set when the set side 6002 is at a binary one level at the output terminal and the reset side 6004 at a binary zero at the output terminal thereof. The output at the reset side is fed through a gate 6006 and a second gate 6008 to a program emitter inhibit output conductor 5462. A binary one level signal on the program emitter inhibit conductor 5462 provides the inhibit function for the program emitter section, specifically the counter 5312, to inhibit any input signals thereto. Also, the output of gate 6008 is provided to conductor 5852 by means of a conductor 6012 to inhibit the outputs of all of the function gates in this portion of the control system.

At such time as the home button described above, is actuated, the binary one output signal from the reset side 5838 of flip-flop 5770 is fed to the input to gate 6006 by means of a conductor 6016 and also this binary one signal is fed to a manual entry gate 6018 and an automatic on gate 6020 by means of a conductor 6022. Thus, when the program home circuit is being utilized, the manual entry and automatic-on circuit is disabled due to the plurality of inhibit signals fed thereto by the reset side of the program home flip-flop unit 5770. When the letter H is sensed at the vertical reader unit, the home flip-flop 5770 is switched back to its normal conditions and the inhibit is removed from the program emitter inhibit circuit. The initial condition of flip-flop 5980 is set from a signal impressed on conductor 4326 connected to the grounding circuit of FIGURE 26, and the signal is impressed on conductor 5846 and an RC coupling circuit 6028 to set the flip flop unit 5980.

When it is desired to provide a manual entry into the system, a manual entry norgate 6030 is provided with an input signal from the nand gates to a plurality of input terminal 6032. The output of gate 6030 is provided to the gate 6018 which, if all input conductors are at a binary zero level, provides a binary one to an RC coupling circuit 6034. The output pulse from coupling circuit 6034 sets the conditions in the flip-flop unit 5980 to provide an inhibit signal at the output conductor 5462. Similarly, when an "automatic-on" signal is provided at the output of the nand gates, it is impressed on the "automatic-on" norgate 6038 by means of a plurality of input terminals 6040. The output of gate 6038 is fed to the reset side 6004 of flip-flop 5980 by means of the gate 6020 and an RC coupling circuit 6044. Thus, the inhibit signal is removed from the program emitter inhibit output conductor 5462 and also from the function output gate described in conjunction with FIGURES 48 and 49.

The particular operation of the format control system has been provided with an automatic entry into the automatic-on condition by the user operating the tab key. Accordingly, when the user is typing into the manual keyboard and it is desired to enter into automatic operation of the format control system, the user presses the tab key to shift the carriage mechanism to the next operating position on the sheet of paper. Accordingly, the output of gate 3030 (FIGURE 28) is fed to the input conductor 6050 to provide an input to the flip-flop unit 5980 by means of a pair of gates 6052, 6054 and an RC coupling circuit 6056. Thus, the flip-flop unit 5980 is reset to provide a binary zero output at conductor 5462 to remove the inhibit signals from the program emitter section and the output function gates.

Referring back to the FCS on-off switch, the output terminal of the reset side 5932 of flip-flop unit 5902 is fed to a space inhibit circuit 6060, by means of a conductor 6062, which is adapted to correlate the spacing function with the operation of the total format control system. The spacing function in the normal typewriter machine is

considerably faster than the signals may be propagated to the rest of the system, particularly the format control system. Accordingly, it is necessary to inhibit the triggering of the control loop by means of the space output flip-flop unit in the typewriter output logic (FIGURE 28). The output signal on conductor 6062 is fed to the input of a gate 6066, which is fed to the input of a space gate unit 6068, through a conductor 6070. The input signal from the conductor 6062 is also fed to a second space gate 6072 by means of conductor 6074. The gate 6088 receives its input signal from the space flip-flop unit in the typewriter output section, the gate being connected thereto by means of a conductor 6076 connected to the set side 2966 of the flip-flop 2968.

The input to gate 6072 is provided from the typewriter output space gate 2960 by means of a conductor 2698 which receives an output signal from the space pickup coil 2958 through the gate 2960. It is to be understood that the input to gate 6068 is delayed by approximately 20 milliseconds as compared to the input to gate 6072. This delay is inherent in the use of the RC coupling circuit 2964 due to the fact that the trailing edge of the pulse is utilized to set the conditions of flip-flop unit 2968. As stated above, this circuit has been provided to incorporate the delay in providing a pulse to cycle the control loop, the cycling pulse being fed to gate 2674 by means of a conductor 2700 (FIGURE 45).

When the FCS on-off switch has been actuated to turn the format control system on, a binary one signal is fed by means of conductor 6062, directly to the input to gate 6072. Accordingly, the output of this gate is inhibited and the first pulse from the space pickup coil is not passed through to the gate 2674 to cycle the control loop 2114. However, this binary one signal on conductor 6062 is inverted by gate 6066 to provide an input of binary zero to gate 6068 by means of the conductor 6070. Accordingly, the delay pulse on input conductor 6076 will pass through gate 6068 to cycle the control loop in a manner similar to that described in conjunction with the description of FIGURE 26. The output of gate 6066 is also fed to the input of gate 5265 by means of a conductor 6071 to inhibit the horizontal reader strobe pulse from one shot multivibrator 5256 during the period when the main reader unit is on and it is desired to inhibit the operation of the FCS horizontal reader.

In certain situations, it is desired to utilize various coded signals to perform a plurality of functions. One such situation occurs when the system has been programmed to print a character on receipt of the stop code, as for example, to print the letter "a" when the stop code is read on the tape. When the "stop" code is read, a reader clutch signal is generated, the trailing edge of which generates a reader logic strobe shot. The "stop" signal is passed through the logic and an "a" is also printed. As outlined above, a strobe channel signal is generated by the sprocket hole or one of the channel holes and, if this signal were not inhibited, the system would synchronize on this strobe channel signal.

Accordingly, it is desired to inhibit the strobe channel shot until such time as a tape advance signal is received from the tape advance pickup (FIGURE 26) by means of conductor 6086. When a "reader stop" signal is received at the input terminals 5712 of gate 5710 (FIGURE 48), the output signal is fed to the stop flip-flop 5717 (FIGURE 45) by means of the conductor 5719. This signal switches the flip-flop 5717 from a binary one at its set side 6087 to a binary zero, thereby switching the reset side 6089 to a binary one. This binary one is fed to the input to a gate 6091 by means of a conductor 6093. The gate 6091 also receives an inhibit signal from gate 6066 through the conductor 6070 and a conductor 6097 to inhibit the output of gate 6091 at such time as a binary one signal appears at the output of gate 6066. The reader clutch will produce another output signal, this signal being the desired synchronizing signal, which produces an output

signal on conductor 6086. This signal is fed to the reset side 6089 of flip-flop 5717 by a conductor 6103 to reset the flip-flop 5717 and remove the inhibit from gate 6091. The output signal from gate 6091 is impressed on a grounding circuit 6105, which is fed to conductor 6086. Accordingly, the control loop is synchronized with the operation of the reader, as is the normal situation.

In certain other situations, as when the carriage return function is performed, the carriage mechanism is not positively stopped but rather is overdriven by the inertia of the mechanism. In view of the fact that the strobe signal from the strobe channel is generated in response to the movement of the tape through the horizontal reader and the reader is directly connected to movement of the carriage mechanism, this "jiggling" may cause a succession of several signals to be generated. According, once the first strobe signal is received, it is necessary to inhibit any further signals to be passed through the system from the horizontal reader until such time as the carriage mechanism has come to rest. To this end, a single shot multivibrator 6113 is connected to the output of gate 6084 by means of a conductor 6115 and an RC coupling circuit 6117 whereby the trailing edge of the initial strobe signal triggers the single shot multivibrator 6113. The output of the multivibrator 6113 is fed, through a diode 6121 and a conductor 6123, to conductor 5265 to inhibit the output of gate 5261. The output of single shot multivibrator 6113 is of sufficient duration to insure that the carriage mechanism has come to a complete stop.

In the operation of the format control system wherein the auxiliary control system (the vertical and horizontal reader units) are controlling the operation of the writing system, a tape advance signal is not generated to provide a cycling pulse for the reader control loop 2414. Accordingly, a simulated tape advance signal is generated by the single shot multivibrator 5257, described above, and this signal is passed through a gate 6084 and thence to the input to gate 2407 (FIGURE 26) by means of a conductor 6086 and grounding circuit 6105. Thus, the operation of the reader control loop is maintained during the portion of the program wherein the format control system is providing automatic signals to the typewriter unit. In order to insure that the format control system is turned on, an inhibit signal is provided by means of the conductor 6070 and a diode 6088 and conductor 6090 to one of the input terminals of the gate 5261. Accordingly, if the format control system switch 5900 has not been actuated to the "on" position, a binary zero level signal will be present on conductor 6062 and a binary one signal on conductor 6070. Accordingly, the input to gate 5261 will be inhibited and the pulse to single shot multivibrator 5256 will not be provided to simulate the tape advance signal on conductor 6086.

Certain other commonly utilized functions are provided in a plurality of gates such as space, the period, tab, upper shift, lower shift, slash, asterisk and hyphen, which receive input signals from outputs of the "nand" gates 5300. The input signals are fed to a plurality of gates 6096 by input terminals 6094. The output signals from the gates 6096 are connected to input conductors in the typewriter input logic which correspond to the particular functions or characters being performed or imprinted, respectively. Accordingly, a plurality of output terminals 6098 receive the output signals from gates 6096 through a plurality of inhibit gates 6100. These functions are inhibited by the inhibit signal described above and impressed on conductor 5852 during the operation of the system.

Referring now to FIGURE 50, there is illustrated a plurality of digit switches 6110 to 6124 which are adapted to receive input signals from the output terminals 5414 of the diode matrix circuit 5316 or nand gates 5300. For purposes of simplicity only one digit switch 6110 has been illustrated and it is to be understood that

the remainder of the digital switches 6112 to 6124 are identical in circuit configuration and operation to that of the switch portion 6134 of digit switch 6110. Specifically digit switch 6110 is provided with an input signal to one of a plurality of input terminals 6128, the signal being fed to a plurality of output norgates 6132 through a multiposition switch 6134. The switch 6134 is provided with an armature blade 6136 which is adapted to be selectively moved into contact with a plurality of terminals 6138. The selective energization of one of the terminals 6138 will energize one of the norgates 6132 through a plurality of conductors 6170, thus providing a preselected output configuration. The norgates 6132 are interconnected with the input conductors of the plurality of gates 1570 to 1588 (FIGURE 23), thereby actuating a certain code of interposers of the typewriter unit, wherein the output signals are fed by a plurality of inverter gates 6142, diode 6144 and output conductors 6146. It is to be understood that each of the output conductors 6146 energizes a particular combination of interposers to represent individual characters to be typed and the user may preprogram a particular code into the writing system by presetting each of the switches 6134.

Each one of the remaining digital switches 6112 to 6124 are provided with output conductors which may be interconnected with the remainder of the input conductors 6172 to 6184 to each of the gates 6132. Accordingly, the first conductor of switch 6112 will be connected to input conductor 6172, the first conductor of switch 6114 to input conductor 6174 and so forth. Also, the second conductors of each switch 6112 to 6124 are connected to the second gate 6132, as described in conjunction with the interconnections with the first gate 6132. A space gate 6150 is provided having a plurality of input terminals 6152 which are also connected to the output terminals of the diode matrix section 5316. The output of gate 6150 is fed to a space output conductor 6154 which is connected to the space input hub 6510 (FIGURE 25) through an inverter gate 6156 and a diode 6158. The outputs of the plurality of gates 6142 and 6156 are simultaneously fed to the typewriter input logic by means of a strobing signal impressed on a conductor 6160. The signal is generated in the reader control circuit and the current level in the conductor 6160 is raised by means of a plurality of emitter follower circuits 6162, connected thereto.

While it will be apparent that the preferred embodiments of the invention disclosed are well calculated to fulfill the objects above stated, it will be appreciated that the invention is susceptible to modification, variation and change without departing from the proper scope or fair meaning of the subjoined claims.

What is claimed is:

1. A writing system utilizing coded information input means coded in accordance with any one of a plurality of first codes, and an information output means having means actuated in accordance with a second code comprising means for generating information signals in accordance with the information in said input means, a first plurality of gate means responsive to said signal generating means for producing first output signals in accordance with the first code of information signals, a second plurality of gate means responsive to said first output signals for producing second output signals in accordance with the second code, means selectively interconnecting said first gate means and said second gate means for producing output information in said information output means representative of the information coded in the input means, and means coupling said second gate means to the information output means.

2. A writing system utilizing coded information input means coded in accordance with any one of a plurality of first codes, and an information output means having means actuated in accordance with a second code comprising means for generating information signals in ac-

cordance with the information in said input means, a first plurality of interconnected norgates responsive to said signal generating means for producing first output signals in accordance with the first code of information signals, a second plurality of norgates having input terminals selectively connected to said output signals of said first plurality of norgates for producing second output signals in accordance with the second code, means selectively interconnecting the output of said first plurality of interconnected norgates and said second plurality of interconnected norgates for producing output information in said information output means representative of the information coded in the output means, and means coupling said second plurality of norgates to the information output means.

3. A writing system utilizing coded information input means coded in accordance with any one of a plurality of first codes, and an information output means having means actuated in accordance with a second code comprising means for generating discrete groups of information signals, each group being related to at least one character of information in accordance with the characters of information in said input means, first logic means responsive to each of said groups of information signals of said signal generating means for producing first output signals in accordance with the first code of information signals, second logic means responsive to said first logic output signal for producing second output signals in accordance with the second code, means selectively interconnecting said first logic means and said second logic means for producing output information in said information output means representative of the information coded in the input means, and means coupling said second logic means to the information output means.

4. A writing system utilizing coded information input means coded in accordance with any one of a plurality of first codes and an information output means having means actuated in accordance with a second code comprising means for generating discrete groups of information signals, each group being related to at least one character of information in accordance with the characters of information in said input means, a first plurality of interconnected norgates responsive to said signal generating means for producing first output signals in accordance with the first code of information signals, each of said first output signals being representative of one of said groups of information signals, a second plurality of norgates having input terminals selectively connected to said output signal of said first plurality of norgates for producing second output signals in discrete groups of information signals in accordance with the second code, means selectively interconnecting said first and second plurality of norgates for producing output information in said information output means representative of the information coded in the input means and means coupling said second plurality of norgates to the information output means.

5. A writing system utilizing coded information storage input means coded in accordance with any one of a plurality of first codes and a typewriter output means having means actuated in accordance with any one of a plurality of second code comprising reader means for generating information signals in accordance with the information contained in said input means, first logic means for producing first output signals in accordance with the first code in said information storage input means, second logic means responsive to said first logic output signals for producing second output signals in accordance with the second code, means selectively interconnecting said first logic means and said second logic means for producing output information in the typewriter means being representative of the information coded in the information storage means, and means coupling said second logic means to the typewriter means.

6. A writing system utilizing coded information stor-

age input means coded in accordance with any one of a plurality of first codes and a typewriter output means having means actuated in accordance with any one of a plurality of second codes comprising reader means for generating information signals in accordance with the information contained in said input means, a first plurality of interconnected norgates responsive to said signal generating means for producing first output signals in accordance with the first code of the information storage input means, a second plurality of norgates having input terminals selectively connected to said output signals of said first plurality of norgates for producing second output signals in accordance with the second code, means selectively interconnecting said first logic means and said second plurality of norgates and said second plurality of norgates for producing output information in the typewriter means representative of the information coded in the information storage means, and means coupling said second plurality of norgates to the typewriter means.

7. A writing system utilizing coded information storage input means coded in accordance with any one of a plurality of first codes and a typewriter output means having means actuated in accordance with any one of a plurality of second codes comprising reader means for generating discrete groups of information signals, each group being related to at least one character of information in accordance with the characters of information in said input means, first logic means for producing first output signals in accordance with the first code in the information storage input means, each of said first output signals being representative of at least one group of said information signals, second logic means responsive to said first logic output signals for producing second output signals in accordance with the second code, means selectively interconnecting said first logic means and said second logic means for producing output information in the typewriter means representative of the information coded in the information storage means, and means coupling said second logic means to the typewriter means.

8. A writing system utilizing coded information storage input means coded in accordance with any one of a plurality of first codes and a typewriter output means in accordance with any one of a plurality of second codes comprising means generating discrete groups of information signals, each group being related to at least one character of information in accordance with the characters of information in said input means, a plurality of bistable coupling means having its stable states responsive to the information signal of each discrete group, a first plurality of interconnected norgates responsive to said bistable coupling means for producing first output signals, each set of output signals being generated in accordance with the first code of discrete groups of information signals of the information storage input means, a second plurality of norgates having input terminals selectively connected to said output signals of said first plurality of norgates for producing second output signals in accordance with the second code, means interconnecting said first logic means and said second logic means for producing output information in the typewriter means representative of the information coded in the information storage means, and means coupling said second logic means to the typewriter means.

9. A writing system utilizing coded information storage input means including a plurality of channels coded in accordance with any one of a plurality of first codes and a typewriter output means in accordance with any one of a plurality of second codes comprising means generating discrete groups of information signals, each group being related to at least one character of information in accordance with the characters of information in said input means, a plurality of flip flop units associated with the input channels having a first normal stable state and a second stable state responsive to the information signal of each discrete group, a first plurality of interconnected norgates responsive to the output of the flip flop units for producing first output signals in accordance with the first code in the information storage input means, second logic means responsive to said first logic output signals for producing second output signals in accordance with the second code, means selectively interconnecting said first logic means and said second logic means for producing output information in the typewriter means being representative of the information coded in the information storage means, and means coupling said second logic means to the typewriter means.

gates responsive to both states of said bistable coupling means for producing first output signals, each set of output signals being generated in accordance with the first code of discrete groups of information signals of the information storage input means, a second plurality of norgates having input terminals selectively connected to said output signals of said first plurality of norgates for producing second output signals in accordance with the second code, means selectively interconnecting said first logic means and said second logic means for producing output information in the typewriter means representative of the information coded in the information storage means, and means coupling said second logic means to the typewriter means.

10. A writing system utilizing typewriter means producing coded information signals in accordance with any one of a plurality of first codes and a coded information storage output means coded in accordance with any one of a plurality of second codes comprising means for generating information signals in response to the actuation of portions of the typewriter means, first logic means responsive to said generating means for producing first output signals in accordance with the first code of information signals, second logic means responsive to said first logic output signals for producing second output signals in accordance with the second code, means interconnecting said first and second logic means for producing output information in the coded information storage output means representative of the information in the typewriter means, and means coupling said second logic means to the storage output means.

11. A writing system utilizing typewriter means producing coded information signals in accordance with any one of a plurality of first codes and a coded information storage output means coded in accordance with any one of a plurality of second codes comprising means for generating information signals in response to actuation of portions of the typewriter means, a first plurality of interconnected norgates responsive to said signal generating means for producing first output signals in accordance with the first code of information signals, a second plurality of norgates having input terminals collectively connected to said output signal of said first plurality of norgates for producing second output signals in accordance with the second code, means selectively interconnecting said first and second plurality of norgates for producing output information in the coded information storage output means representative of the information in the typewriter means, and means coupling said second plurality of norgates to the storage output means.

12. A writing system utilizing typewriter means producing coded information signals in accordance with any one of a plurality of first codes and a coded information storage output means coded in accordance with any one of a plurality of second codes comprising means for generating discrete groups of information signals, each group being related to at least one character of information in accordance with the characters of information in the typewriter means, first logic means responsive to said generating means for producing first output signals in accordance with the first code of information signals, each of said first output signals being generated in accordance with each of said discrete groups of information signals, second logic means responsive to said first logic output signals for producing second output signals in accordance with the second code, means selectively interconnecting said first and second logic means for producing output information in the coded information storage output means being representative of the information in the typewriter means, and means coupling said second logic means to the storage output means.

13. A writing system utilizing typewriter means producing coded information signals in accordance with any one of a plurality of first codes and a coded information storage output means coded in accordance with any

one of a plurality of second codes comprising means for generating discrete groups of information signals in response to actuation of portions of the typewriter means, each group being related to at least one character of information in accordance with the characters of information in the typewriter means, a first plurality of interconnected norgates responsive to said signal generating means for producing first output signals in accordance with the first code of information signals, each of said first output signals being generated in accordance with each of said discrete groups of information signals, a second plurality of norgates having input terminals collectively connected to said output signals of said first plurality of norgates for producing second output signals in accordance with the second code, means selectively interconnecting said first and second plurality of norgates for producing output information in the coded information storage output means being representative of the information in the typewriter means, and means coupling said second logic means to the storage output means.

14. A writing system utilizing typewriter means producing coded information signals in accordance with any one of a plurality of first codes and a coded information storage output means coded in accordance with any one of a plurality of second codes comprising means for generating information signals in response to the actuation of portions of the typewriter means, first logic means responsive to said generating means for producing first output signals in accordance with the first code of information signals, said output signals being in a binary form and designated in accordance with the decimal equivalent of said first binary output signals, second logic means responsive to said first logic output signals for producing second output signals of a binary form in accordance with the second code, said second logic means having input terminals therein designated in accordance with the decimal equivalent of said second binary output signals, means selectively interconnecting said first and second logic means in accordance with said decimal designation for producing output information in the coded information storage output means representative of the information in the typewriter means, and means coupling said second logic means to the storage output means.

15. A writing system utilizing coded information storage input means coded in accordance with any one of a plurality of first codes, a typewriter output means having means actuated in accordance with any one of a plurality of second codes, the typewriter means producing coded information signals in accordance with any one of a plurality of third codes and a coded information storage output means coded in accordance with any one of a plurality of fourth codes comprising reader means for generating discrete groups of information signals, each group being related to at least one character of information in accordance with the characters of information in said input means, first logic means for producing first output signals in accordance with the first code in the information storage input means, each of said first output signals being representative of at least one group of said information signals, second logic means responsive to said first logic output signals for producing second output signals in accordance with the second code, means selectively interconnecting said first logic means and said second logic means for producing output information in the typewriter means representative of the information coded in the information storage means, and means coupling said second logic means to the typewriter means, typewriter signal means for generating discrete groups of information signals, each group being related to at least one character of information in accordance with the characters of information in the typewriter means, third logic means responsive to said signal generating means for producing third output signals in accordance with the third code of information signals, each of said third output signals being generated in accordance with each of said discrete groups

of information signals, fourth logic means responsive to said third logic output signals for producing fourth output signals in accordance with the fourth code, means selectively interconnecting said third and fourth logic means for producing output information in the coded information storage output means being representative of the information in the typewriter means, and means coupling said second logic means to the storage output means.

16. A control circuit for a writing system or the like comprising, input circuit means generating synchronizing signals in response to operations of the writing system, loop circuit means for generating a signal about said loop circuit means in response to said synchronizing signals, and output circuit means for synchronizing the operations of the writing system in response to said loop signal.

17. The control circuit of claim 16 wherein said input circuit means includes gate circuit means and said writing system operations generate a plurality of signals, said gate circuit means generating an output signal in accordance with a coincidence of predetermined conditions in at least two of said plurality of signals.

18. The control circuit of claim 16 wherein said loop circuit includes first pulse producing means for producing a first pulse in response to said loop signal and second pulse producing means for producing a second pulse in response to said loop signal, said second pulse being delayed in time from said first pulse.

19. The control circuit of claim 16 wherein the writing system includes a reader unit for reading coded input information having a clutch and an input storage logic circuit connected to the reader unit having an output circuit, said first pulse operating to permit the reader unit to read the coded input information and said second pulse enabling the storage logic circuit to produce an output signal in the output circuit.

20. A control circuit for a writing system or the like comprising, logic circuit means generating synchronizing signals in response to operations of the writing system including function and character printing operations, loop circuit means for generating a signal about said loop circuit means in response to said synchronizing signals, and output circuit means including strobe means for synchronizing the operations of the writing system in response to said loop signal.

21. A control circuit for a writing system or the like comprising, input circuit means generating synchronizing signals in response to operations of the writing system including means sensing the completion of functions of the writing system and means sensing the printing of characters, loop circuit means for generating a signal about said loop circuit means in response to said synchronizing signals, and output circuit means for synchronizing the operations of the writing system in response to said loop signal.

22. The control circuit of claim 21 wherein said input circuit means includes gate circuit means and said writing system operations generate a plurality of signals, said gate circuit means generating an output signal in accordance with a coincidence of predetermined conditions in at least two of said plurality of signals.

23. The control circuit of claim 21 wherein said loop circuit includes first pulse producing means for producing a first pulse in response to said loop signal and second pulse producing means for producing a second pulse in response to said loop signal, said second pulse being delayed in time from said first pulse.

24. The control circuit of claim 21 wherein the writing system includes a reader unit for reading coded input information having a clutch and an input storage logic circuit connected to the reader unit having an output circuit, said first pulse operating to permit the reader unit to read the coded input information and said second pulse enabling the storage logic circuit to produce an output signal in the output circuit.

25. A control circuit for a writing system or the like

having a reader unit containing a clutch means comprising, input circuit means generating synchronizing signals in response to operations of the writing system including means sensing the completion of functions of the writing system and means sensing the printing of characters, loop circuit means for generating a signal about said loop circuit means in response to said synchronizing signals, and output circuit means for synchronizing the operations of the writing system in response to said loop signal including strobe circuit means for strobing information contained in one portion of the writing system to another portion thereof and clutch circuit means for advancing the clutch means of the reader unit.

15. The control circuit of claim 25 wherein said input circuit means includes gate circuit means and said writing system operations generate a plurality of signals, said gate circuit means generating an output signal in accordance with a coincidence of predetermined conditions in at least two of said plurality of signals.

20. 26. The control circuit of claim 25 wherein said loop circuit includes first pulse producing means for producing a first pulse in response to said loop signal and second pulse producing means for producing a second pulse in response to said loop signal, said second pulse being delayed in time from said first pulse.

25. 27. The control circuit of claim 25 wherein said loop circuit includes first pulse producing means for producing a first pulse in response to said loop signal and second pulse producing means for producing a second pulse in response to said loop signal, said second pulse being delayed in time from said first pulse.

30. 28. A control circuit for a writing system or the like including a reader unit for reading information stored in a coded information input means and a typewriter unit having cycling means therein for comprising, input circuit means generating synchronizing signals in response to operations of the writing system including first circuit means generating a signal in response to movement of the coded information input means in the reader unit and second circuit means generating a signal in response to movement of the cycling means in the typewriter unit, loop circuit means for generating a signal about said loop circuit means in response to predetermined conditions of said first and second circuit means, output circuit means for synchronizing the operations of the writing system in response to said loop signal.

35. 29. The control circuit of claim 28 wherein said first circuit means includes first magnetic pickup means generating a first pulse in response to the movement and first bistable storage means storing said first pulse, and said second circuit means includes second magnetic pickup means generating a second pulse and second bistable storage means storing said second pulse.

40. 30. The control circuit of claim 29 wherein said predetermined conditions are the states of said first and second bistable storage means.

45. 31. The control circuit of claim 30 wherein said loop circuit includes first pulse producing means for producing a first pulse in response to said loop signal and second pulse producing means for producing a second pulse in response to said loop signal, said second pulse being delayed in time from said first pulse.

50. 32. The control circuit of claim 30 wherein said loop circuit includes gate means to generate the loop signal in response to the coincidence of the same states in said first and second bistable storage means.

55. 33. A control circuit for a writing system or the like including a reader unit for reading information stored in a coded information input means and a typewriter unit having cycling means therein for comprising, circuit means generating synchronizing signals in response to operations of the writing system including first circuit means generating a signal in response to movement of the coded information input means in the reader unit and second circuit means generating a signal in response to movement of the cycling means in the typewriter unit, loop circuit means for generating a signal which traverses said loop circuit means in response to predetermined conditions of said first and second circuit means, said 60. synchronizing signals, output circuit means for syn-

125

chronizing the operations of the writing system in response to said loop signal, said loop circuit means including means for resetting the initial conditions of said loop circuit means in response to the completion of the passage of said loop circuit signal about said loop circuit means.

34. The control circuit of claim 33 wherein said first circuit means includes first magnetic pickup means generating a first pulse in response to the movement and first bistable storage means storing said first pulse, and said second circuit means includes second magnetic pickup means generating a second pulse and second bistable storage means storing said second pulse.

35. The control circuit of claim 34 wherein said predetermined conditions are the states of said first and second bistable storage means.

36. The control circuit of claim 35 wherein said loop circuit includes first pulse producing means for producing a first pulse in response to said loop signal and second pulse producing means for producing a second pulse in response to said loop signal, said second pulse being delayed in time from said first pulse.

37. The control circuit of claim 35 wherein said loop circuit includes gate means to generate the loop signal in response to the coincidence of the same states in said first and second bistable storage means.

38. A control circuit for a writing system or the like comprising, circuit means generating synchronizing signals in response to operations of the writing system, loop circuit means for generating a signal about said loop circuit means in response to said synchronizing signals, strobe circuit means for synchronizing the operation of certain portions of the writing system in response to said loop circuit signal and output circuit means for synchronizing the operation of certain other portions of the writing system in response to said loop circuit signal.

39. A control circuit for a writing system or the like comprising, first circuit means for generating first control signals in response to the operation of certain writing system functions, second circuit means for generating second control signals in response to the completion of certain other writing machine functions, loop circuit means for generating a signal about said loop circuit means in response to at least one of said first and second control signals, strobe circuit means for synchronizing the operation of certain portions of the writing system in response to said loop circuit signal and output circuit means for synchronizing the operation of certain other portions of the writing system in response to said loop circuit signal.

40. A control circuit for a writing system or the like comprising, first circuit means for generating first control signals in response to the operation of certain writing system functions, second circuit means for generating second control signals in response to the completion of certain other writing machine functions, means for correlating said first and second control signals and generating a third control signal in response to predetermined conditions in said first and second circuit means, loop circuit means for generating a signal about said loop circuit means in response to said third control signal, strobe circuit means for synchronizing the operation of certain portions of the writing system in response to said loop circuit signal and output circuit means for synchronizing the operation of certain other portions of the writing system in response to said loop circuit signal.

41. The control circuit of claim 40 wherein said correlating means includes gate means, said third control signal corresponding to a coincidence of substantially the same signal level from said first and second circuit means.

42. The control circuit of claim 41 wherein said loop circuit includes first pulse producing means for producing a first pulse in response to said loop signal and second pulse producing means for producing a second pulse in response to said loop signal, said second pulse being delayed in time from said first pulse.

126

43. The control circuit of claim 42 wherein the writing system includes a reader unit for reading coded input information having a clutch and an input storage logic circuit connected to the reader unit having an output circuit, said first pulse operating to permit the reader unit to read the coded input information and said second pulse enabling the storage logic circuit to produce an output signal in the output circuit.

44. A control circuit for a writing system or the like including a reader unit having coded information input means adapted to be passed therethrough and a typewriter unit having movable actuation means therein comprising, first signal generating means for generating first control signals in response to the passage of the information input means through the reader unit, second circuit means for generating second control signals in response to the movement of the typewriter actuation means, third circuit means for generating a third control signal in response to the existence of predetermined electrical conditions in said first and second circuit means, loop circuit means for generating a signal about said loop circuit means in response to said third control signal, strobe circuit means for synchronizing the operation of certain portions of the writing system in response to said loop circuit signal and output circuit means for synchronizing the operation of certain other portions of the writing system in response to said loop circuit signal.

45. The control circuit of claim 44 wherein said first circuit means includes first magnetic pickup means generating a first pulse in response to the movement and first bistable storage means storing said first pulse, and said second circuit means includes second magnetic pickup means generating a second pulse and second bistable storage means storing said second pulse.

46. The control circuit of claim 45 wherein said loop circuit includes gate means to generate the loop signal in response to the coincidence of the same states in said first and second bistable storage means.

47. A control circuit for a writing system or the like including a reader unit having coded information input means adapted to be passed therethrough and a typewriter unit having movable actuation means therein comprising, first circuit means for generating first control signals in response to the completion of certain writing system functions, second circuit means for generating second control signals in response to the passage of the information input means through the reader unit, third circuit means for generating third control signals in response to the movement of the typewriter actuation means, fourth circuit means for generating a fourth control signal in response to the existence of a coincidence of predetermined electrical conditions in said second and third circuit means, loop circuit means for generating a signal about said loop circuit means in response to one of said first and fourth control signals, and output circuit means for synchronizing the operation of certain portions of the writing system in response to said loop circuit signal.

48. The control circuit of claim 47 wherein said second circuit means includes first magnetic pickup means generating a first pulse in response to the movement and first bistable storage means storing said first pulse, and third circuit means includes second magnetic pickup means generating a second pulse and second bistable storage means storing said second pulse.

49. The control circuit of claim 48 wherein said loop circuit includes gate means to generate the loop signal in response to the coincidence of the same states in said first and second bistable storage means.

50. The control circuit of claim 48 wherein said loop circuit means includes means for resetting the initial conditions of said loop circuit means in response to the completion of the passage of said loop circuit signal about said loop circuit means.

51. A control circuit for a writing system or the like including a reader unit having coded information input means adapted to be passed therethrough and a type-

writer unit having movable actuation means therein comprising, first circuit means for generating first control signals in response to the completion of certain writing system functions, second circuit means for generating second control signals in response to the passage of the information input means through the reader unit, third circuit means for generating third control signals in response to the movement of the typewriter actuation means, fourth circuit means for generating a fourth control signal in response to the existence of a coincidence of predetermined electrical conditions in said second and third circuit means, loop circuit means for generating a signal about said loop circuit means in response to one of said first and fourth control signals, strobe circuit means for synchronizing the operation of certain portions of the writing system in response to said loop circuit signal and output circuit means for synchronizing the operation of certain other portions of the writing system in response to said loop circuit signal.

52. A control circuit for a writing system or the like including a reader unit having coded information input means adapted to be passed therethrough and a typewriter unit having movable actuation means therein comprising, first circuit means for generating first control signals in response to the completion of certain writing system functions, second circuit means for generating second control signals in response to the passage of the information input means through the reader unit, third circuit means for generating third control signals in response to the movement of the typewriter actuation means, fourth circuit means for generating a fourth control signal in response to the operation of certain other writing system functions, fifth circuit means for generating a fifth control signal in response to one of said third and fourth control signals, sixth circuit means for generating a six control signal in response to a coincidence of predetermined electrical conditions in said second and fifth circuit means, loop circuit means for generating a signal about said loop circuit means in response to one of said first and sixth control signals, strobe circuit means for synchronizing the operation of certain portions of the writing system in response to said loop circuit signal and output circuit means for synchronizing the operation of certain other portions of the writing system in response to said loop circuit signal.

53. The control circuit of claim 52 including means for inhibiting the operation of the loop circuit means during certain operations of the writing system.

54. The control circuit of claim 53 wherein said inhibit means comprises a grounding circuit grounding one of said control signals in response to signals generated in said writing system.

55. A control circuit for a writing system or the like including a reader unit having coded information input means adapted to be passed therethrough and a typewriter unit having movable actuation means therein comprising, first circuit means including first norgate means for generating first control signals in response to the completion of certain writing system functions, second circuit means including motion sensing means for generating second control signals in response to the passage of the information input means through the reader unit, third circuit means including motion sensing means for generating third control signals in response to the movement of the typewriter actuation means, fourth circuit means including second norgate means for generating a fourth control signal in response to the operation of certain other writing system functions, fifth circuit means for generating a fifth control signal in response to one of said third and fourth control signals from said motion sensing means and said second norgate means, sixth circuit means for generating a six control signal in response to a coincidence of predetermined electrical conditions in said second and fifth circuit means, loop circuit means for generating a signal about said loop circuit means.

circuit means in response to one of said first and sixth control signals, strobe circuit means for synchronizing the operation of certain portions of the writing system in response to said loop circuit signal and output circuit means for synchronizing the operation of certain other portions of the writing system in response to said loop circuit signal.

56. A control circuit for a writing system or the like including a reader unit having coded information input means adapted to be passed therethrough and a typewriter unit having movable actuation means therein comprising, first circuit means for generating first control signals in response to the completion of certain writing system functions, second circuit means for generating second control signals in response to the passage of the information input means through the reader unit, third circuit means for generating third control signals in response to the movement of the typewriter actuation means, fourth circuit means for generating a fourth control signal in response to the operation of certain other writing system functions, fifth circuit means for generating a fifth control signal in response to one of said third and fourth control signals, sixth circuit means for generating a six control signal in response to a coincidence of predetermined electrical conditions in said second and fifth circuit means, loop circuit means including means for inhibiting said loop circuit means in response to turning off the control circuit for generating a signal about said loop circuit means in response to one of said first and sixth control signals, strobe circuit means for synchronizing the operation of certain portions of the writing system in response to said loop circuit signal, output circuit means for synchronizing the operation of certain other portions of the writing system in response to said loop circuit signal, and an on-off circuit for said loop circuit means including pulse producing means, bistable storage means connected to said pulse producing means for producing an inhibiting output signal in response to an output pulse from said pulse producing means, and means connecting said inhibiting output signal to said loop circuit inhibiting means.

57. A control circuit for a writing system or the like including a reader unit having coded information input means adapted to be passed therethrough and a typewriter unit having movable actuation means therein comprising, first circuit means for generating first control signals in response to the completion of certain writing system functions, second circuit means for generating second control signals in response to the passage of the information input means through the reader unit, third circuit means for generating third control signals in response to the movement of the typewriter actuation means, fourth circuit means for generating a fourth control signal in response to the operation of certain other writing system functions, fifth circuit means for generating a fifth control signal in response to one of said third and fourth control signals, sixth circuit means for generating a six control signal in response to a coincidence of predetermined electrical conditions in said second and fifth circuit means, loop circuit means including means for inhibiting said loop circuit means in response to turning off the control circuit for generating a signal about said loop circuit means in response to one of said first and sixth control signals, strobe circuit means for synchronizing the operation of certain portions of the writing system in response to said loop circuit signal, output circuit means for synchronizing the operation of certain other portions of the writing system in response to said loop circuit signal, and an on-off circuit for said loop circuit means including pulse producing means, bistable storage means connected to said pulse producing means for producing an inhibiting output signal in response to an output pulse from said pulse producing means, and means connecting said inhibiting output signal to said loop circuit inhibiting means, said signal in said loop circuit.

cuit means being connected to reset the initial conditions in said loop circuit.

58. A control circuit for a writing system or the like including a reader unit having coded information input means adapted to be passed therethrough and a typewriter unit having movable actuation means therein comprising, first logic circuit means including norgate means having inputs from various function sensing means of the system for generating first control signals in response to the completion of certain writing system functions, second circuit means including bistable storage means and magnetic pickup means responsive to movement of portions of the reader unit for generating second control signals in response to the passage of the information input means through the reader unit, third circuit means including bistable storage means and magnetic pickup means for generating third control signals in response to the movement of the typewriter actuation means, fourth circuit means including norgate means having inputs from various function actuating circuits for generating a fourth control signal in response to the presence of signals actuating certain other writing system functions, fifth circuit means for generating a fifth control signal in response to one of said third and fourth control signals, sixth circuit means for generating a six control signal in response to a coincidence of predetermined electrical conditions in said second and fifth circuit means, loop circuit means for generating a signal about said loop circuit means in response to one of said first and sixth control signals, strobe circuit means for synchronizing the operation of certain portions of the writing system in response to said loop circuit signal, and output circuit means for synchronizing the operation of certain other portions of the writing system in response to said loop circuit signal.

59. A control circuit for a writing system or the like including a reader unit having coded information input means adapted to be passed therethrough and a typewriter unit having movable actuation means therein comprising, first logic circuit means including norgate means having inputs from various function sensing means of the system for generating first control signals in response to the completion of certain writing system functions, second circuit means including bistable storage means and magnetic pickup means responsive to movement of portions of the reader unit for generating second control signals in response to the passage of the information input means through the reader unit, third circuit means including bistable storage means and magnetic pickup means for generating third control signals in response to the movement of the typewriter actuation means, fourth circuit means including norgate means having inputs from various function actuating circuits for generating a fourth control signal in response to the presence of signals actuating certain other writing system functions, fifth circuit means for generating a fifth control signal in response to one of said third and fourth control signals, sixth circuit means for generating a six control signal in response to a coincidence of predetermined electrical conditions in said second and fifth circuit means, loop circuit means for generating a signal about said loop circuit means in response to one of said first and sixth control signals, strobe circuit means for synchronizing the operation of certain portions of the writing system in response to said loop circuit signal, said loop circuit means including means for resetting the initial conditions of said loop circuit means in response to the completion of the passage of said loop circuit signal about said loop circuit means.

60. A control circuit for a writing system or the like including a reader unit having coded information input means adapted to be passed therethrough and a typewriter unit having movable actuation means therein comprising, first logic circuit means including norgate means having inputs from various function sensing means of the

system for generating first control signals in response to the completion of certain writing system functions, second circuit means including bistable storage means and magnetic pickup means responsive to movement of portions of the reader unit for generating second control signals in response to the passage of the information input means through the reader unit, third circuit means including bistable storage means and magnetic pickup means for generating third control signals in response to the movement of the typewriter actuation means, fourth circuit means including norgate means having inputs from various function actuating circuits for generating a fourth control signal in response to the presence of signals actuating certain other writing system functions, fifth circuit means including bistable storage circuit means for generating a fifth control signal in response to one of said third and fourth control signals, sixth circuit means including loop circuit norgate means having first and second inputs including said second and sixth control signals for generating a six control signal in response to a coincidence of predetermined electrical conditions in said second and fifth circuit means, loop circuit means for generating a signal about said loop circuit means in response to one of said first and sixth control signals, strobe circuit means for producing an output pulse to synchronize the operation of certain logic portions of the writing system in response to said loop circuit signal and output pulse circuit means producing an output pulse preceding said strobe pulse in time for synchronizing the operation of the reader unit in response to said loop circuit signal.

61. The control circuit of claim 60 wherein said loop circuit means is closed on itself and said loop circuit signal resets the initial conditions of said loop circuit means on the completion of the loop circuit signal about said loop circuit means.

62. A control circuit for a writing system or the like including a reader unit having coded information input means adapted to be passed therethrough and a typewriter unit having movable actuation means therein and logic circuit means interconnecting the reader unit and the typewriter unit comprising, first logic circuit means including norgate means having inputs from various function sensing means of the system for generating first control signals in response to the completion of certain writing system functions, second circuit means including bistable storage means and magnetic pickup means responsive to movement of portions of the reader unit for generating second control signals in response to the passage of the information input means through the reader unit, third circuit means including bistable storage means and magnetic pickup means for generating third control signals in response to the movement of the typewriter actuation means, fourth circuit means including norgate means having inputs from various function actuating circuits for generating a fourth control signal in response to the presence of signals actuating certain other writing system functions, fifth circuit means for generating a fifth control signal in response to one of said third and fourth control signals, sixth circuit means for generating a six control signal in response to a coincidence of predetermined electrical conditions in said second and fifth circuit means, loop circuit means for generating a signal about said loop circuit means in response to one of said first and sixth control signals including first and second monostable pulse producing circuits, said second monostable circuit being triggered by said first monostable device, strobe circuit means including means connected to the logic circuit means for passing coded information forward through the logic circuit means on a leading edge of a pulse produced by said second monostable circuit and resetting certain portions of the logic circuit means on the trailing edge of said pulse, and output circuit means for synchronizing the operation of the reader unit in response to said loop circuit signal.

63. A control circuit for a writing system or the like including a reader unit having coded information input

means adapted to be passed therethrough and a typewriter unit having movable actuation means therein comprising, first circuit means including first norgate means for generating first control signals in response to the completion of certain writing system functions, second circuit means including motion sensing means for generating second control signals in response to the passage of the information input means through the reader unit, third circuit means including motion sensing means for generating third control signals in response to the movement of the typewriter actuation means, fourth circuit means including second norgate means for generating a fourth control signal in response to the operation of certain other writing system functions, fifth circuit means for generating a fifth control signal in response to one of said third and fourth control signals from said motion sensing means and said second norgate means, sixth circuit means for generating a six control signal in response to a coincidence of predetermined electrical conditions in said second and fifth circuit means, loop circuit means for generating a signal about said loop circuit means in response to one of said first and sixth control signals including first and second monostable pulse producing circuits, said second monostable circuit being triggered by said first monostable device, strobe circuit means including means connected to the logic circuit means for passing coded information forward through the logic circuit means on a leading edge of a pulse produced by said second monostable circuit and resetting certain portions of the logic circuit means on the trailing edge of said pulse, and output circuit means for synchronizing the operation of the reader unit in response to said loop circuit signal.

64. A control circuit for a writing system or the like including a reader unit having coded information input means adapted to be passed therethrough and a typewriter unit having movable actuation means therein comprising, first logic circuit means including norgate means having inputs from various function sensing means of the system for generating first control signals in response to the completion of certain writing system functions, second circuit pickup means responsive to movement of portions of the reader unit for generating second control signals in response to the passage of the information input means through the reader unit, third circuit means including bistable storage means and magnetic pickup means for generating third control signals in response to the movement of the typewriter actuation means, fourth circuit means including norgate means having inputs from various function actuating circuits for generating a fourth control signal in response to the presence of signals actuating certain other writing system functions, fifth circuit means for generating a fifth control signal in response to one of said third and fourth control signals, sixth circuit means for generating a six control signal in response to a coincidence of predetermined electrical conditions in said second and fifth circuit means, loop circuit means for generating a signal about said loop circuit means in response to one of said first and sixth control signals including first and second monostable pulse producing circuits, said second monostable circuit being triggered by said first monostable device, strobe circuit means including means connected to the logic circuit means for passing coded information forward through the logic circuit means on a leading edge of a pulse produced by said second monostable circuit and resetting certain portions of the logic circuit means on the trailing edge of said pulse, and output circuit means for synchronizing the operation of the read unit in response to said loop circuit signal.

65. A control circuit for a writing system or the like including a reader unit having coded information input means adapted to be passed therethrough and a typewriter unit having movable actuation means therein comprising, first logic circuit means including norgate means having inputs from various function sensing means of the system for generating first control signals in response

to the completion of certain writing system functions, second circuit means including bistable storage means and magnetic pickup means responsive to movement of portions of the reader unit for generating second control signals in response to the passage of the information input means through the reader unit, third circuit means including bistable storage means and magnetic pickup means for generating third control signals in response to the movement of the typewriter actuation means, fourth circuit means including norgate means having inputs from various function actuating circuits for generating a fourth control signal in response to the presence of signals actuating certain other writing system functions, fifth circuit means for generating a fifth control signal in response to one of said third and fourth control signals, sixth circuit means for generating a six control signal in response to a coincidence of predetermined electrical conditions in said second and fifth circuit means, loop circuit means for generating a signal about said loop circuit means in response to one of said first and sixth control signals, including first and second monostable pulse producing circuits, said second monostable circuit being triggered by said first monostable device, strobe circuit means including means connected to the logic circuit means for passing coded information forward through the logic circuit means on a leading edge of a pulse produced by said second monostable circuit and resetting certain portions of the logic circuit means on the trailing edge of said pulse, and output circuit means for synchronizing the operation of the reader unit in response to said loop circuit signal.

66. In combination with an information recorder input means and a reproducer means, a recorder input logic means for storing coded input signals in response to coded information signals from said recorder input means, reproducer input logic means for providing input information signals to said reproducer means in response to information signals stored in said recorder logic means, said recorder input logic means including enabling means for transferring the information stored in said recorder input logic means to said reproducer input logic means, and control circuit logic means for enabling said enabling means including means responsive to signals generated in one of said logic means for generating a control signal, and pulse generating means for generating and feeding a strobe pulse to said enabling means in response to said control signal.

67. In combination with an information recorder input means and a reproducer means, a recorder input logic means for storing coded input signals in response to coded information signals from said recorder input means, reproducer input logic means for providing input information signals to said reproducer means in response to information signals stored in said recorder logic means, said recorder input logic means including enabling means for transferring the information stored in said recorder input logic means to said reproducer input logic means, and control circuit logic means for enabling said enabling means and advancing the operation of the information input means including means responsive to signals generated in one of said logic means for generating a control signal, first pulse generating means for impressing a pulse on said information input means in response to said control signal and second pulse generating means for generating and feeding a strobe pulse to said enabling means in response to said control signal.

68. In combination with an information recorder input means and a reproducer means, a recorder input logic means for storing coded input signals in response to coded information signals from said recorder input means, reproducer input logic means for providing input information signals to said reproducer means in response to information signals stored in said recorder logic means, said recorder input logic means including enabling means for transferring the information stored in said recorder

133

input logic means to said reproducer input logic means, and a control circuit including input loop circuit means generating synchronizing signals in response to signals impressed on said reproducer input logic means for generating a signal about said loop circuit means in response to said synchronizing signals, and output circuit means for synchronizing the operations of the writing system in response to said loop signal.

69. The control circuit of claim 68 wherein said input circuit means includes gate circuit means and said reproducer input logic means generates a plurality of signals, said gate circuit means generating an output signal in accordance with a coincidence of predetermined conditions in at least two of said plurality of signals.

70. The control circuit of claim 68 wherein said loop circuit includes first pulse producing means for producing a first pulse in response to said loop signal and second pulse producing means for producing a second pulse in response to said loop signal, said second pulse being delayed in time from said first pulse.

71. In combination with an information recorder input means and a reproducer means, a recorder input logic means for storing coded input signals in response to coded information signals from said recorder input means, reproducer input logic means for providing input information signals to said reproducer means in response to information signals stored in said recorder logic means, said recorder input logic means including enabling means for transferring the information stored in said recorder input logic means to said reproducer input logic means, and a control circuit comprising, logic circuit means generating synchronizing signals in response to operations of the writing system including function and character printing operations, loop circuit means for generating a signal about said loop circuit means in response to said synchronizing signals, and output circuit means including strobe means for enabling said enabling means in response to said loop signal.

72. In combination with an information recorder input means and a reproducer means, a recorder input logic means for storing coded input signals in response to coded information signals from said recorder input means, reproducer input logic means for providing input information signals to said reproducer means in response to information signals stored in said recorder logic means, said recorder input logic means including enabling means for transferring the information stored in said recorder input logic means to said reproducer input logic means, and a control circuit comprising, input circuit means generating synchronizing signals in response to operations of the writing system including means sensing the completion of functions of the writing system and means sensing the printing of characters, loop circuit means for generating a signal about said loop circuit means in response to said synchronizing signals, and output circuit means for synchronizing the operations of the writing system in response to said loop signal, said input circuit means includes gate circuit means and said writing system operations generate a plurality of signals, said gate circuit means generating an output signal in accordance with a coincidence of predetermined conditions in at least two of said plurality of signals.

73. The control circuit of claim 72 wherein said loop circuit includes first pulse producing means for producing a first pulse in response to said loop signal and second pulse producing means for producing a second pulse in response to said loop signal, said second pulse being delayed in time from said first pulse.

74. In combination with an information recorder input means and a reproducer means, a recorder input logic means for storing coded input signals in response to coded information signals from said recorder input means, reproducer input logic means for providing input information signals to said reproducer means in response

134

to information signals stored in said recorder logic means, said recorder input logic means including enabling means for transferring the information stored in said recorder input logic means to said reproducer input logic means, and a control circuit including input circuit means generating synchronizing signals in response to operations of the information recorder input means including first circuit means generating a signal in response to movement of a coded information input means in the information recorder input means and second circuit means generating a signal in response to movement of an actuating mechanism in the reproducer means, loop circuit means for generating a signal about said loop circuit means in response to a coincidence of predetermined conditions of said first and second circuit means, output circuit means for synchronizing the operations of the recorder input means and said recorder input logic means in response to said loop signal.

75. The control circuit of claim 74 wherein said first circuit means includes first magnetic pickup means generating a first pulse in response to the movement and first bistable storage means storing said first pulse, and said second circuit means includes second magnetic pickup means generating a second pulse and second bistable storage means storing said second pulse.

76. The control circuit of claim 75 wherein said predetermined conditions are the states of said first and second bistable storage means and said loop circuit includes first pulse producing means for producing a first pulse in response to said loop signal and second pulse producing means for producing a second pulse in response to said loop signal, said second pulse being delayed in time from said first pulse.

77. In combination with an information recorder input means and a reproducer means, a recorder input logic means for storing coded input signals in response to coded information signals from said recorder input means, reproducer input logic means for providing input information signals to said reproducer means in response to information signals stored in said recorder logic means, said recorder input logic means including enabling means for transferring the information stored in said recorder input logic means to said reproducer input logic means, and a control circuit including first circuit means for generating first control signals in response to the operation of certain signals generated in said recorder input logic section, second circuit means for generating second control signals in response to the completion of certain information recorder input means functions, means for correlating said first and second control signals and generating a third control signal in response to predetermined conditions in said first and second circuit means, loop circuit means for generating a signal about said loop circuit means in response to said third control signal, strobe circuit means for synchronizing the operation of certain portions of said recorder input logic means in response to said loop circuit signal and output circuit means for synchronizing the operation of certain information recorder input means in response to said loop circuit signal.

78. The control circuit of claim 77 wherein said correlating means includes gate means, said third control signal corresponding to a coincidence of substantially the same signal level from said first and second circuit means.

79. The control circuit of claim 78 wherein said loop circuit includes first pulse producing means for producing a first pulse in response to said loop signal for pulsing said output circuit means and second pulse producing means for producing a second pulse in response to said loop signal for pulsing said strobe circuit means, said second pulse being delayed in time from said first pulse.

80. In combination with an information recorder input means and a reproducer means, a recorder input logic means for storing coded input signals in response to coded information signals from said recorder input means, re-

135

producer input logic means for providing input information signals to said reproducer means in response to information signals stored in said recorder logic means, said recorder input logic means including enabling means for transferring the information stored in said recorder input logic means to said reproducer input logic means, and a control circuit including first circuit means for generating first control signals in response to the completion of certain reproducer means functions, second circuit means for generating second control signals in response to the passage of information input means through the information recorder input means, third circuit means for generating third control signals in response to the movement of actuation means of the reproducer means, fourth circuit means for generating a fourth control signal in response to the existence of a coincidence of predetermined electrical conditions in said second and third circuit means, loop circuit means for generating a signal about said loop circuit means in response to one of said first and fourth control signals, and output circuit means for synchronizing the operation of certain portions of the information recorder input means and recorder input logic means in response to said loop circuit signal, said first circuit means including first magnetic pickup means generating a first pulse in response to the movement and first bistable storage means storing said first pulse, and said second circuit means includes second magnetic pickup means generating a second pulse and second bistable storage means storing said second pulse, said loop circuit includes gate means to generate the loop signal in response to the coincidence of the same states in said first and second bistable storage means.

81. In combination with an information recorder input means and a reproducer means, a recorder input logic means for storing coded input signals in response to coded information signals from said recorder input means, reproducer input logic means for providing input information signals to said reproducer means in response to information signals stored in said recorder logic means, said recorder input logic means including enabling means for transferring the information stored in said recorder input logic means to said reproducer input logic means, and a control circuit including first circuit means for generating first control signals in response to the completion of certain reproducer means functions, second circuit means for generating second control signals in response to the passage of information input means through the information recorder input means, third circuit means for generating third control signals in response to the movement of actuation means of the reproducer means, fourth circuit means for generating a fourth control signal in response to function signals generated in said recorder input logic means, fifth circuit means for generating a fifth control signal in response to one of said third and fourth control signals, sixth circuit means for generating a six control signal in response to a coincidence of predetermined electrical conditions in said second and fifth circuits means, loop circuit means for generating a signal about said loop circuit means in response to one of said first and sixth control signals, strobe circuit means for synchronizing the operation of certain portions of said recorder input logic means in response to said loop circuit signal and output circuit means for synchronizing the operation of the information recorder input means in response to said loop circuit signals.

82. The control circuit of claim 81 including means for inhibiting the operation of the loop circuit means during certain operations of the writing system, said inhibit means comprising a bistable device generating a signal into said sixth circuit means and a grounding circuit grounding said signals into said sixth circuit means in response to signals generated in said recorder input logic means.

83. A control circuit for a writing system or the like

136

including a reader unit having coded information input means adapted to be passed therethrough and a typewriter unit having movable actuation means therein comprising, first logic circuit means including norgate means having inputs from various function sensing means of the system for generating first control signals in response to the completion of certain writing system functions, second logic circuit means including a bistable flip-flop circuit and magnetic pickup means responsive to movement of portions of the reader unit for generating second control signals in response to the passage of the information input means through the reader unit, said flip-flop circuit being switched from one stable state to the other stable state in response to signals generated in said magnetic pickup means, third logic circuit means including bistable storage means and magnetic pickup means for generating third control signals in response to the movement of the typewriter actuation means, said last named bistable means being switched from a first to a second stable state in response to signals generated in said magnetic pickup means, fourth circuit means including norgate means having inputs from various function actuating circuits for generating a fourth control signal in response to the presence of at least one signal actuating certain other writing system functions, fifth circuit means including said third logic circuit bistable means for generating a fifth control signal in response to one of said third and fourth control signals, sixth circuit means including norgate means having a plurality of input circuits including said second and fifth circuit means for generating a six control signal in response to a coincidence of predetermined electrical conditions in said second and fifth circuit means, loop circuit means for generating a signal about said loop circuit means in response to one of said first and sixth control signals including first and second monostable pulse producing circuits, said second monostable circuit being triggered by said first monostable device, strobe circuit means including means connected to the logic circuit means for passing coded information forward through the logic circuit means on a leading edge of a pulse produced by said second monostable circuit and resetting certain portions of the logic circuit means on the trailing edge of said pulse, and output circuit means including norgate means having a plurality of inputs including the outputs of said first monostable circuit for synchronizing the operation of the reader unit in response to said loop circuit signal.

84. A control circuit for a writing system or the like having logic circuit means comprising, first link circuit means for producing a clutch advancing output signal in response to an input signal from said logic circuit means to advance clutch portions of the writing system, strobe circuit means for strobing information contained in the logic circuit means in response to signals generated in the writing system due to the movement of parts thereof, and resetting link circuit means for resetting portions of the logic circuit means in response to signals generated in said first link circuit means.

85. A control circuit for a writing system or the like having logic circuit means comprising, first link circuit means for producing a clutch advancing output signal in response to an input signal from said logic circuit means to advance clutch portions of the writing system, strobe circuit means for strobing information contained in the logic circuit means in response to signals generated in the writing system due to the movement of parts thereof, and resetting link circuit means generating an output signal which is delayed in time with respect to said clutch advancing output signal for resetting portions of the logic circuit means in response to signals generated in said first link circuit means.

86. A control circuit for a writing system or the like having logic circuit means comprising, first link circuit means having a plurality of input signals from the logic

due to the movement of parts thereof, said strobe circuit bistable circuit means including output signal means connected to said clutch advancing circuit gate means for inhibiting the operation thereof during said strobing, and resetting link circuit means for resetting bistable portions of the logic circuit means comprising second monostable pulse producing circuit means for producing a fourth signal in response to said first signals, second gate means for producing a fifth signal and resetting the certain bistable portions having a plurality of inhibit input circuits including fourth inhibit means for inhibiting said resetting signal in response to one state of said first clutch advancing circuit bistable means and said first inhibit means, said second gate means connected to said strobe circuit bistable means for changing the state thereof from the set to the reset state.

99. A control circuit for a writing system or the like having logic circuit means including a plurality of gate circuits and bistable circuits and an error signal producing circuit comprising, first link circuit means including input gate means having a plurality of input signals from the logic circuit means for producing a first output signal in response to at least one of said input signals, monostable pulse producing means for producing a second signal in response to said first signal, inverter means for inverting said second signal, first gate means for producing a third signal in response to said inverted signal having first inhibit means for inhibiting said third signal in response to signals produced in certain modes of operation of the writing system, second inhibit means for inhibiting said third signal in response to signals produced in certain other modes of operation of the writing system and third inhibit means for inhibiting said third signal in response to certain error signals produced in the writing system, clutch advancing circuit means including gate means and bistable means for producing first output signals in response to said third signal and advancing the operation of clutch portions of the writing system, strobe circuit means including bistable circuit means for strobing information contained in certain portions of the writing system in response to signals generated in the writing system due to the movement of parts thereof, said strobe circuit bistable circuit means including output signal means connected to said clutch advancing circuit gate means for inhibiting the operation thereof during said strobing, and resetting link circuit means for resetting bistable portions of the logic circuit means comprising second monostable pulse producing circuit means for producing a fourth signal in response to said first signals, second gate means for producing a fifth signal and resetting the certain bistable portions having a plurality of inhibit input circuits including fourth inhibit means for inhibiting said resetting signal in response to one state of said first clutch advancing circuit bistable means and said first inhibit means, said second gate means connected to said strobe bistable means for changing the state thereof from the set to the reset state.

100. A control circuit for a writing system or the like having a typewriter, a punch unit logic circuit means including a plurality of gate circuits and bistable circuits and an error signal producing circuit comprising, first link circuit means including input norgate means having a plurality of inputs from the logic circuit means for producing a first output signal of a binary one level in response to at least one of said inputs, monostable pulse producing means including coupling circuit means generating a spike pulse for producing a second signal of specified duration in response to said first signal, inverter means including a common emitter transistor for inverting said second signal, first norgate means for producing a third signal in response to said inverted signal having a first inhibiting input signal for inhibiting said third signal in response to signals produced in certain modes of

operation of the writing system wherein the punch is turned off, a second inhibiting input signal for inhibiting said third signal in response to signals produced in certain other modes of operation of the writing system and a third inhibiting input signal for inhibiting said third signal in response to certain error signals produced in the writing system in response to an error in parity in the logic circuit means, and clutch advancing circuit means including norgate means and bistable means for producing first output signals in response to said third signal and advancing the operation of clutch portions of the punch unit, strobe circuit means including bistable circuit means for strobing information contained in certain portions of the logic circuit means in response to signal generated in the writing system due to the movement of parts of the typewriter, said strobe circuit bistable circuit means including output signal means connected to said clutch advancing circuit norgate means for inhibiting the operation thereof during said strobing, and resetting link circuit means for resetting bistable portions of the logic circuit means comprising second monostable pulse producing circuit means for producing a fourth signal in response to said first signals, second gate means for producing a fifth signal and resetting the certain bistable portions having a plurality of inhibit input circuits including fourth inhibit means for inhibiting said resetting signal in response to one state of said first clutch advancing circuit bistable means and said first inhibit means, said second gate means connected to said strobe circuit bistable means for changing the state thereof from the set to the reset state.

101. In combination with a reproduced means actuatable to produce an output information record and a coded information output means, a reproducer output logic means for storing coded information input signals in response to the actuation of said reproducer means, coded information output logic means for storing coded information in response to the stored signals in said reproducer output logic means including output enabling means for transferring the information stored in said coded information output logic means to said coded information output means, said reproducer output logic means including enabling means for transferring the information stored in said reproducer output logic means to said coded information output logic means, and control circuit means including means connected to said enabling means for producing output signals to enable said enabling means.

102. In combination with a reproducer means actuatable to produce an output information record and an advanceable coded information output means, a reproducer output logic means for storing coded information input signals in response to the actuation of said reproducer means, coded information output logic means for storing coded information in response to the stored signals in said reproducer output logic means including output enabling means for transferring the information stored in said coded information output logic means to said coded information output means, said reproducer output logic means including enabling means for transferring the information stored in said reproducer output logic means to said coded information output logic means, and control circuit means including means connected to said enabling means for producing output signals to enable said enabling means, and pulse producing means responsive to signals produced in said control circuit means for advancing the coded information output means.

103. In combination with a reproducer means actuatable to produce an output information record and a coded information output means, a reproducer output logic means for storing coded information input signals in response to the actuation of said reproducer means, coded information output logic means for storing coded information in response to the stored signals in said reproducer output logic means including output enabling means for trans-

ferring the information stored in said coded information output logic means to said coded information output means, said reproducer output logic means including enabling means for transferring the information stored in said reproducer output logic means to said coded information output logic means, and a control circuit comprising first link circuit means for producing a clutch advancing output signal in response to an input signal from said coded information output logic means to advance clutch portions of the writing system, strobe circuit means for strobing information contained in the logic circuit means in response to signals generated in the reproducer means due to the movement of parts thereof, and resetting link circuit means for resetting portions of the logic circuit means in response to signals generated in said first link circuit means.

104. In combination with a reproducer means actuatable to produce an output information record and a coded information output means, a reproducer output logic means for storing coded information input signals in response to the actuation of said reproducer means, coded information output logic means for storing coded information in response to the stored signals in said reproducer output logic means including output enabling means for transferring the information stored in said coded information output logic means to said coded information output means, said reproducer output logic means including enabling means for transferring the information stored in said reproducer output logic means to said coded information output logic means, and a control circuit comprising first link circuit means having a plurality of input signals from the logic circuit means for producing a clutch advancing output signal in response to at least one of said input signals to advance clutch portions of the writing system, strobe circuit means for strobing information contained in said reproducer output logic means in response to signals generated in the reproducer means due to the movement of parts thereof, and resetting link circuit means for resetting portions of the logic circuit means.

105. In combination with a reproducer means actuatable to produce an output information record and a coded information output means, a reproducer output logic means for storing coded information input signals in response to the actuation of said reproducer means, coded information output logic circuit means for storing coded information in response to the stored signals in said reproducer output logic means including output enabling means for transferring the information stored in said coded information output logic means to said coded information output means, said reproducer output logic means including enabling means for transferring the information stored in said reproducer output logic means to said coded information output logic means, and a control circuit comprising first link circuit means including gate circuit means having a plurality of input signals from said coded information logic circuit means and first monostable pulse producing means for producing a clutch advancing output signal of a predetermined duration in response to at least one of said input signals to advance clutch portions of the writing system, strobe circuit means for strobing information contained in the logic circuit means in response to signals generated in the writing system due to the movement of parts thereof, and resetting link circuit means generating an output signal which is delayed in time with respect to said clutch advancing output signal for resetting portions of the logic circuit means in response to signals generated in said first link circuit means.

106. In combination with a reproducer means actuatable to produce an output information record and a coded information output means, a reproducer output logic means for storing coded information input signals in response to the actuation of said reproducer means, coded information output logic means for storing coded information in response to the stored signals in said reproducer output logic means including bistable means and output enabling means for transferring the information stored in said

coded information output logic means to said coded information output means, said reproducer output logic means including bistable circuit means and enabling means for transferring the information stored in said reproducer output logic means to said coded information output logic means, an error signal producing circuit for producing an error signal in response to a parity check of signals in said coded information output logic means, and a control circuit having first link circuit means including input gate means having a plurality of input signals from said coded information output logic means for producing a first output signal in response to at least one of said input signals, monostable pulse producing means for producing a second signal in response to said first signal, inverter means for inverting said second signal, first gate means for producing a third signal in response to said inverted signal, clutch advancing circuit means including gate means for producing first output signals in response to said third signal and advancing the operation of clutch portions of the coded information output means, strobe circuit means for strobing information contained in certain portions of said reproducer output logic means in response to signals generated in the reproducer means due to the movement of parts thereof, and resetting link circuit means for resetting bistable portions of the logic circuit means comprising second monostable pulse producing circuit means for producing a fourth signal in response to said first signals, second gate means for producing a fifth signal and resetting the certain bistable portions having a plurality of inhibit input circuits.

107. In combination with a reproducer means actuatable to produce an output information record and a coded information output means, a reproducer output logic means for storing coded information input signals in response to the actuation of said reproducer means, coded information output logic means for storing coded information in response to the stored signals in said reproducer output logic means including bistable means and output enabling means for transferring the information stored in said reproducer output logic means to said coded information output logic means, an error signal producing circuit for producing an error signal in response to a parity check of signals in said coded information output logic means, and a control circuit having first link circuit means including input gate means having a plurality of input signals from said coded information output logic means for producing a first output signal in response to at least one of said input signals, monostable pulse producing means for producing a second signal in response to said first signal, inverter means for inverting said second signal, first gate means for producing a third signal in response to said inverted signal having first inhibit means for inhibiting said third signal in response to signals produced in certain modes of operation of the writing system, second inhibit means for inhibiting said third signal in response to signals produced in certain other modes of operation of the writing system and third inhibit means for inhibiting said third signal in response to said error signals produced in said error producing circuit, clutch advancing circuit means including gate means and bistable means for producing first output signals in response to said third signal and advancing the operation of clutch portions of the coded information output means, strobe circuit means including bistable circuit means for strobing information contained in certain portions of said coded information output means in response to signals generated in the reproducer means due to the movement of parts thereof, said strobe circuit bistable circuit means including output signal means connected to said clutch advancing circuit gate means for inhibiting the operation thereof during said

145

strobing, and resetting link circuit means for resetting bistable portions of the logic circuit means comprising second monostable pulse producing circuit means for producing a fourth signal in response to said first signals, second gate means for producing a fifth signal and resetting the certain bistable portions having a plurality of inhibit input input circuits including fourth inhibit means for inhibiting said resetting signal in response to one state of said first clutch advancing circuit bistable means and said first inhibit means, said second gate means connected to said strobe circuit bistable means for changing the state thereof from the set to the reset state.

108. A method of printing particular information at particular locations on a sheet of paper utilizing an automatic writing system comprising the steps of: mounting a sheet of paper in a typewriter, causing relative displacement of the sheet of paper in the typewriter from line to line, moving a data storage device linearly in step by step fashion in direct relationship to the indexing movement of the sheet of paper in the typewriter, causing relative displacement of a printing mechanism from printing space to printing space, moving another data storage device linearly in step by step fashion in direct relationship to spacing movement of the printing mechanism relative to the sheet of paper, generating a signal on each data storage device at each line and each printing space on the sheet of paper where information is to be printed, and programming the writing system to perform preselected operations at predetermined printing spaces.

109. A method of printing particular information at particular locations on a sheet of paper utilizing an automatic writing system comprising the steps of: mounting a sheet of paper in a typewriter, causing relative displacement of the sheet of paper in the typewriter from line to line, moving a data storage device linearly in step by step fashion in direct relationship to indexing movement of the sheet of paper in the typewriter, causing relative displacement of a printing mechanism from printing space to printing space, moving another data storage device linearly in step by step fashion in direct relationship to spacing movement of the printing mechanism relative to the sheet of paper, generating a signal on each data storage device at each line and each printing space on the sheet of paper where information is to be printed, digitally coordinating the signals generated by the data storage devices to generate a control signal and utilizing said control signal to perform preselected operations at predetermined printing spaces.

110. A method of printing particular information at particular locations on a sheet of paper utilizing an automatic writing system comprising the steps of: mounting a sheet of paper in a typewriter, automatically homing the sheet of paper to a preselected start position, causing relative displacement of the sheet of paper in the typewriter from line to line, moving a data storage device linearly in step by step fashion in direct relationship to indexing movement of the sheet of paper in the typewriter, moving another data storage device linearly in step by step fashion in direct relationship to spacing movement of the type head relative to the sheet of paper, generating a signal on each data storage device at the beginning of all places on the sheet of paper where information is to be printed, digitally coordinating the signals generated on each data storage device, and programming the automatic writing system to perform pre-programmed operations at preselected printing spaces in response to the digitally coordinated signals.

111. A method of printing particular information at particular locations on a sheet of paper utilizing an automatic writing system comprising the steps of: mounting a sheet of paper in a typewriter, causing relative displacement of the sheet of paper in the typewriter from line to line, moving a data storage device linearly in step by step fashion in direct relationship to indexing movement of the sheet of paper in the typewriter, moving another data stor-

146

age device linearly in step by step fashion in direct relationship to spacing movement of the type head relative to the sheet of paper, generating a signal on each data storage device at the beginning of all places on the sheet of paper where information is to be printed, feeding the generated signals from the data storage devices to a coordinating circuit, generating a digital control signal for each printing space on the sheet of paper, and automatically operating the writing system through a plurality of sequential operations in response to the digital control signal.

112. A method of printing particular information at particular locations on a sheet of paper utilizing an automatic writing system comprising the steps of: mounting a sheet of paper in a typewriter, causing relative displacement of the sheet of paper in the typewriter from line to line, moving a data storage device linearly in step by step fashion in direct relationship to indexing movement of the sheet of paper in the typewriter, moving another data storage device linearly in step by step fashion in direct relationship to spacing movement of the type head relative to the sheet of paper, generating a signal on each data storage device at the beginning of all places on the sheet of paper where information is to be printed, feeding the generated signals from the data storage devices to a coordinating circuit, generating a digital control signal for each printing space on the sheet of paper, feeding preselected control signals to at least one of sequentially advancing timing circuit and a switching circuit, and automatically operating the writing system in response to signals fed to the timing circuit and the switching circuit.

113. A method of printing particular information at particular locations on a sheet of paper utilizing an automatic writing system comprising the steps of: mounting a sheet of paper in a typewriter, causing relative displacement of the sheet of paper in the typewriter from line to line, moving a data storage device linearly in step by step fashion in direct relationship to indexing movement of the sheet of paper in the typewriter, moving another data storage device linearly in step by step fashion in direct relationship to spacing movement of the type head relative to the sheet of paper, generating a signal on each data storage device at the beginning of all places on the sheet of paper where information is to be printed, feeding the generated signals from the data storage devices to a coordinating circuit, generating a digital control signal for each printing space on the sheet of paper, feeding preselected control signals to at least one of a sequentially advancing timing circuit and a switching circuit, generating a plurality of timed signals in synchronism with certain portions of said writing system when control signals are fed to said timing circuit, and automatically operating the writing system in response to signals fed to the timing circuit and the switching circuit.

114. A method of printing particular information at particular locations on a sheet of paper utilizing an automatic writing system comprising the steps of: mounting a sheet of paper in a typewriter, energizing a homing circuit and generating indexing and carriage return signals, feeding said indexing and carriage return signals to operative portions of the writing system to initially position the paper in the typewriter, causing relative displacement of the sheet of paper in the typewriter from line to line, moving a data storage device linearly in step by step fashion in direct relationship to indexing movement of the sheet of paper in the typewriter, moving another data storage device linearly in step by step fashion in direct relationship to spacing movement of the type head relative to the sheet of paper, generating a signal on each data storage device at the beginning of all places on the sheet of paper where information is to be printed, feeding the generated signals from the data storage devices to a coordinating circuit, generating a digital con-

147

trol signal for each printing space on the sheet of paper, feeding preselected control signals to at least one of a sequentially advancing timing circuit and a switching circuit, generating a plurality of timed signals in synchronism with certain portions of said writing system when control signals are fed to said timing circuit, and automatically operating the writing system in response to signals fed to the timing circuit and the switching circuit.

115. The method of programming an automatic writing system to fill in data on blanks provided on a sheet of paper having a particular format comprising the steps of; mounting an ordinant tape for movement in direct relationship to vertical displacement of said sheet of paper from line to line on the paper, mounting an abscissa tape for movement in direct relationship to relative horizontal displacement between the sheet of paper and the typing mechanism along any given line, and advancing the position of said typing head relative to said sheet of paper in step by step fashion to the beginning of each of the various blanks and coding the ordinant and abscissa tapes at each such blank with a reference code indicative of that particular location on the sheet of paper, and filling in the blank spaces with data selected from suitable storage devices by signals generated by said ordinant and abscissa tapes at each of said blank spaces.

116. The method of programming an automatic writing system to fill in data on blanks provided on a sheet of paper having a particular format comprising the steps of; mounting an ordinant tape for movement in direct relationship to vertical displacement of said sheet of paper on a platen from line to line on the paper, mounting an abscissa tape for movement in direct relationship to relative horizontal displacement between the sheet of paper and the typing head along any given line, homing the typing head and platen to an initial known position of said typing head and the platen relative to said sheet of paper and advancing the position of said typing head relative to said sheet of paper in step by step fashion to the beginning of each of the various blanks and coding the ordinant and abscissa tapes at each such blank with a reference code indicative of that particular location on the sheet of paper, and filling in the blank spaces with data selected from suitable storage devices by signals generated by said ordinant and abscissa tapes at each of said blank spaces.

117. A format control system for automatically controlling the operation of an automatic writing system including a typewriter unit having a platen and a carriage mechanism comprising, means for sensing the line-by-line position of the platen in the typewriter including means generating a first coded control signal in accordance therewith, means for sensing the step-by-step position of the character imprinting mechanism relative to the platen including means generating a second coded control signal in accordance therewith, circuit means for translating said first and second coded signals into first and second output signals, means digitally coordinating said first and second output signals for producing a controlling output signal in accordance with preselected individual combinations of said first and second output signals, and preprogrammed means for automatically controlling the operation of the writing system in response to said controlling output signal.

118. A format control system for automatically controlling the operation of an automatic writing system including a typewriter unit having a platen and a carriage mechanism comprising, means for sensing the line-by-line position of the platen in the typewriter including means generating a first coded control signal in accordance therewith, means for sensing the step-by-step position of the character imprinting mechanism relative to the platen including means generating a second coded control signal in accordance therewith, first and second logic circuit means for translating said first and second coded signals

65
70
75

148

into first and second output signals, respectively, means digitally coordinating said first and second output signals for producing a controlling output signal in accordance with preselected combinations of said first and second output signals, and preprogrammed means for automatically controlling the operation of the writing system in response to said controlling output signal.

119. A format control system for automatically controlling the operation of an automatic writing system including a typewriter unit having a platen and a carriage mechanism comprising first reader means for sensing the line-by-line position of the platen in the typewriter including means generating a first train of coded control signals in accordance therewith, second reader means for sensing the step-by-step position of the character imprinting mechanism relative to the platen including means generating a second train of coded control signals in accordance therewith, first and second logic circuit means for translating said first and second coded signals into first and second character output signals, respectively, means digitally coordinating said first and second output signals for producing a digital output signal in accordance with preselected combinations of said first and second output signals, and means for automatically controlling the operation of the writing system in response to said controlling output signal.

120. A format control system for automatically controlling the operation of an automatic writing system including a typewriter unit having a platen and a carriage mechanism comprising first reader means for sensing the line-by-line position of the platen in the typewriter including means generating a first train of coded control signals in accordance therewith, second reader means for sensing the step-by-step position of the character imprinting mechanism relative to the platen including means generating a second train of coded control signals in accordance therewith, first and second logic circuit means for translating said first and second coded signals into first and second character output signals, respectively, means digitally coordinating said first and second output signals for producing a digital output signal in accordance with preselected combinations of said first and second output signals, and means for automatically controlling the operation of the writing system in response to said controlling output signal including digital switching means having a plurality of programmable outputs, the outputs of said digital switching means operating to print characters in accordance with a preselected program.

121. A format control system for automatically controlling the operation of an automatic writing system including a typewriter unit having a platen and a carriage mechanism comprising first reader means for sensing the line-by-line position of the platen in the typewriter including means generating a first train of coded control signals in accordance therewith, second reader means for sensing the step-by-step position of the character imprinting mechanism relative to the platen including means generating a second train of coded control signals in accordance therewith, first and second logic circuit means for translating said first and second coded signals into first and second character output signals, respectively, means digitally coordinating said first and second output signals for producing a digital output signal in accordance with preselected combinations of said first and second output signals, and means for automatically controlling the operation of the writing system in response to said controlling output signal including a plurality of first gate circuit means, the outputs of said first gate means being connected to operative portions of said typewriter, said first gate circuit means including inhibit means for inhibiting the operation of said first gate circuit means during preselected portions of the operation of said writing system, and programmable switching means connected to the input of the typewriter for producing character imprinting control signals.

122. A format control system for automatically controlling the operation of an automatic writing system including a typewriter unit having a platen and a carriage mechanism comprising, means for sensing the line-by-line position of the platen in the typewriter and generating a first coded control signal in accordance therewith, means for sensing the step-by-step position of the character imprinting mechanism relative to the platen and generating a second coded control signal in accordance therewith, first and second logic circuit means for translating said first and second coded signals into first and second character output signals, respectively, means digitally coordinating said first and second output signals for producing a controlling output signal for each preselected printing space of said writing system in accordance with preselected combinations of said first and second output signals, homing circuit means responsive to an input signal for initially prepositioning said platen with respect to said carriage mechanism including homing switch means for generating a start pulse, circuit means for initiating sufficient carriage return and indexing function to home the relation between the platen and carriage mechanism, and means for automatically controlling the operation of the writing system in response to said controlling output signal.

123. A format control system for automatically controlling the operation of an automatic writing system including a typewriter unit having a platen and a carriage mechanism comprising, first reader means for sensing the line-by-line position of the platen in the typewriter including means generating a first train of coded control signals in accordance therewith, second reader means for sensing the step-by-step position of the character imprinting mechanism relative to the platen including means generating a second train of coded control signals in accordance therewith, first and second logic circuit means for translating said first and second coded signals into first and second character output signals, respectively, means digitally coordinating said first and second output signals for producing a digital output signal for each preselected printing space of said writing system in accordance with preselected combinations of said first and second output signals, homing circuit means responsive to an input signal for initially prepositioning said platen with respect to said carriage mechanism including homing switch means for generating a start pulse, circuit means for initiating sufficient carriage return and indexing function to home the relation between the platen and carriage mechanism, and means for automatically controlling the operation of the writing system in response to said controlling output signal including digital switching means having a plurality of programmable outputs, the outputs of said digital switching means operating to print characters in accordance with a preselected program.

124. A format control system for automatically controlling the operation of an automatic writing system including a typewriter unit having a platen and a carriage mechanism comprising, first reader means for sensing the line-by-line position of the platen in the typewriter including means generating a first train of coded control signals in accordance therewith, second reader means for sensing the step-by-step position of the character imprinting mechanism relative to the platen including means generating a second train of coded control signals in accordance therewith, first and second logic circuit means for translating said first and second coded signals into first and second character output signals, respectively, means digitally coordinating said first and second output signals for producing a digital output signal for each preselected printing space of said writing system in accordance with preselected combinations of said first and second output signals, homing circuit means responsive to an input signal for initially prepositioning said platen with respect to said carriage mechanism including homing switch means for generating a start pulse, circuit means for initiating sufficient carriage return and indexing function to home the relation between the platen and carriage mechanism, and means for automatically controlling the operation of the writing system in response to said controlling output signal, including matrix circuit means having a plurality of lines of successive circuit elements, each of said lines having first circuit elements arranged a first column including a first column of output terminals enabling means connected to said first column for enabling said first output terminals, selective ones of said digitally coordinating means being connected to said enabling means for selectively activating said enabling means, and timed circuit means associated with each of said lines of circuit elements for sequentially pulsing said output terminals in accordance with an input pulse.

relation between the platen and carriage mechanism, and means for automatically controlling the operation of the writing system in response to said controlling output signal including a plurality of first gate circuit means, the outputs of said first gate means being connected to operative portions of said typewriter, said first gate circuit means including inhibit means for inhibiting the operation of said first gate circuit means during preselected portions of the operation of said writing system, and programmable switching means connected to the input of the typewriter for producing character imprinting control signals.

125. A format control system for automatically controlling the operation of an automatic writing system including a typewriter unit having a platen and a carriage mechanism comprising, means for sensing the line-by-line position of the platen in the typewriter and generating a first coded control signal in accordance therewith, means for sensing the step-by-step position of the character imprinting mechanism relative to the platen and generating a second coded control signal in accordance therewith, first and second logic circuit means for translating said first and second coded signals into first and second output signals, respectively, means digitally coordinating said first and second output signals for producing a controlling output signal in accordance with preselected combinations of said first and second output signals, and means for automatically sequentially controlling the operation of the writing system in response to said controlling output signal including matrix circuit means having a plurality of lines of successive circuit elements, each of said lines having first circuit elements arranged a first column including a first column of output terminals enabling means connected to said first column for enabling said first output terminals, selective ones of said digitally coordinating means being connected to said enabling means for selectively activating said enabling means, and timed circuit means associated with each of said lines of circuit elements for sequentially pulsing said output terminals in accordance with an input pulse.

126. A format control system for automatically controlling the operation of an automatic writing system including a typewriter unit having a platen and a carriage mechanism comprising, means for sensing the line-by-line position of the platen in the typewriter and generating a first coded control signal in accordance therewith, means for sensing the step-by-step position of the character imprinting mechanism relative to the platen and generating a second coded control signal in accordance therewith, first and second logic circuit means for translating said first and second coded signals into first and second character output signals, respectively, means digitally coordinating said first and second output signals for producing a controlling output signal for each preselected printing space of said writing system in accordance with preselected combinations of said first and second output signals, homing circuit means responsive to an input signal for initially prepositioning said platen with respect to said carriage mechanism including homing switch means for generating a start pulse, circuit means for initiating sufficient carriage return and indexing function to home the relation between the platen and carriage mechanism, and means for automatically controlling the operation of the writing system in response to said controlling output signal, including matrix circuit means having a plurality of lines of successive circuit elements, each of said lines having first circuit elements arranged a first column including a first column of output terminals enabling means connected to said first column for enabling said first output terminals, selective ones of said digitally coordinating means being connected to said enabling means for selectively activating said enabling means, and timed circuit means associated with each of said lines of circuit elements for sequentially pulsing said output terminals in accordance with an input pulse.

127. A format control system for automatically control-

ling the operation of an automatic writing system including a typewriter unit having a platen and a carriage mechanism comprising, first reader means for sensing the line by line position of the platen in the typewriter including means generating a first train of coded control signals in accordance therewith, second reader means for sensing the step by step position of the character imprinting mechanism relative to the platen including means generating a second train of coded control signals in accordance therewith, first and second logic circuit means for translating said first and second coded signals into first and second character output signals, respectively, means digitally coordinating said first and second output signals for producing a digital output signal for each preselected printing space of said writing system in accordance with preselected combinations of said first and second output signals, homing circuit means responsive to an input signal for initially prepositioning said platen with respect to said carriage mechanism including homing switch means for generating a start pulse, circuit means for initiating sufficient carriage return and indexing function to home the relation between the platen and carriage mechanism, and means for automatically sequentially controlling the operation of the writing system in response to said controlling output signal including matrix circuit means having a plurality of lines of successive circuit elements, each of said lines having first circuit elements arranged a first column including a first column of output terminals enabling means connected to said first column for enabling said first output terminals, selective one of said digitally coordinating means being connected to said enabling means for selectively activating said enabling means, and timed circuit means associated with each of said lines of circuit elements for sequentially pulsing said output terminals in accordance with an input pulse.

128. A format control system for automatically controlling the operation of an automatic writing system including a typewriter unit having a platen and a carriage mechanism comprising, first reader means for sensing the line-by-line position of the platen in the typewriter including means generating a first train of coded control signals in accordance therewith, second reader means for sensing the step-by-step position of the character imprinting mechanism relative to the platen including means generating a second train of coded control signals in accordance therewith, first and second logic circuit means for translating said first and second coded signals into first and second character output signals, respectively, means digitally coordinating said first and second output signals for producing a digital output signal for each preselected printing space of said writing system in accordance with preselected combinations of said first and second output signals, homing circuit means responsive to an input signal for initially prepositioning said platen with respect to said carriage mechanism including homing switch means for generating a start pulse, circuit means for initiating sufficient carriage return and indexing function to home the relation between the platen and carriage mechanism, and means for automatically sequentially controlling the operation of the writing system in response to said controlling output signal including matrix circuit means having a plurality of lines of successive circuit elements, each of said lines having first circuit elements arranged a first column including a first column of output terminals enabling means connected to said first column for enabling said first output terminals, selective ones of said digitally coordinating means being connected to said enabling means for selectively activating said enabling means, and timed circuit means associated with each of said lines of circuit elements for sequentially pulsing said output terminals in accordance with an input pulse.

129. A format control system for automatically controlling the operation of an automatic writing system including a typewriter unit having a platen and a carriage mechanism comprising, ordinate reader means for sens-

ing the line-by-line position of the platen in the typewriter including means generating a first coded control signal in accordance therewith, abscissa reader means for sensing the step-by-step position of the character imprinting mechanism relative to the platen including means generating a second coded control signal in accordance therewith, first and second logic circuit means for translating said first and second coded signals into first and second output signals, respectively, said first and second logic circuit means including bistable storage means for storing said first and second coded signals and first and second norgate circuit means responsively connected to said bistable storage means for translating the information stored in said storage means to said first and second output signals, nand gate means digitally coordinating said first and second output signals for producing a controlling output signal in accordance with preselected combinations of said first and second output signals, and means for automatically controlling the operation of the writing system in response to said controlling output signal.

130. A format control system for automatically controlling the operation of an automatic writing system including a typewriter unit having a platen and a carriage mechanism comprising, means for sensing the line-by-line position of the platen in the typewriter and generating a first coded control signal in accordance therewith, means for sensing the step-by-step position of the character imprinting mechanism relative to the platen and generating a second coded control signal in accordance therewith, first and second logic circuit means for translating said first and second coded signals into first and second output signals, respectively, said first and second logic circuit means including bistable storage means for storing said first and second coded signals and first and second norgate circuit means responsively connected to said bistable storage means for translating the information stored in said storage means to said first and second output signals, nand gate means digitally coordinating said first and second output signals for producing a controlling output signal in accordance with preselected combinations of said first and second output signals, and means for automatically controlling the operation of the writing system in response to said controlling output signal, including matrix circuit means having a plurality of lines of successive circuit elements, each of said lines having first circuit elements arranged a first column including a first column of output terminals enabling means connected to said first column for enabling said first output terminals, selective ones of said digitally coordinating means being connected to said enabling means for selectively activating said enabling means, and timed circuit means associated with each of said lines of circuit elements for sequentially pulsing said output terminals in accordance with an input pulse.

131. A format control system for automatically controlling the operation of an automatic writing system including a typewriter unit having a platen and a carriage mechanism comprising, ordinate reader means for sensing the line-by-line position of the platen in the typewriter including means generating a first coded control signal in accordance therewith, abscissa reader means for sensing the step-by-step position of the character imprinting mechanism relative to the platen including means generating a second coded control signal in accordance therewith, first and second logic circuit means for translating said first and second coded signals into first and second output signals, respectively, said first and second logic circuit means including bistable storage means for storing said first and second coded signals and first and second norgate circuit means responsively connected to said bistable storage means for translating the information stored in said storage means to said first and second output signals, nand gate means digitally coordinating said first and second output signals for producing a controlling output signal in accordance with preselected combinations of said first and second output signals.

153

combinations of said first and second output signals, homing circuit means responsive to an input signal for initially pre-positioning said platen with respect to said carriage mechanism including homing switch means for generating a start pulse, circuit means for initiating sufficient carriage return and indexing function to home the relation between the platen and carriage mechanism, and means for automatically controlling the operation of the writing system in response to said controlling output signal, including matrix circuit means having a plurality of lines of successive circuit elements, each of said lines having first circuit elements arranged a first column including a first column of output terminals enabling means connected to said first column for enabling said first output terminals, selective ones of said digitally coordinating means being connected to said enabling means for selectively activating said enabling means, and timed circuit means associated with each of said lines of circuit elements for sequentially pulsing said output terminals in accordance with an input pulse.

132. The method of homing a carriage and indexing mechanism of an automatic typewriting system comprising the steps of sensing the line by line movement of the indexing mechanism, generating a carriage return signal, actuating the carriage mechanism in response to said carriage return signal, generating a plurality of successive indexing signals, actuating the indexing mechanism in response to said indexing signals, generating an indexing home signal when the indexing mechanism reaches a predetermined indexing position, and ceasing the actuation of the indexing mechanism in response to the indexing home signal.

133. The method of homing a carriage and indexing mechanism of an automatic typewriting system comprising the steps of sensing the line by line movement of the indexing mechanism, generating a carriage return signal, actuating the carriage mechanism in response to said carriage return signal, generating an indexing signal in response to the actuation of the carriage return mechanism, automatically generating a plurality of successive indexing signals, actuating the indexing mechanism in response to said indexing signals, generating an indexing home signal when the indexing mechanism reaches a predetermined indexing position by sensing the line by line movement of the indexing mechanism, and ceasing the actuation of the indexing mechanism in response to the indexing home signal.

134. The method of homing a carriage and indexing mechanism of an automatic typewriting system comprising the steps of sensing the line by line movement of the indexing mechanism and generating a home signal when the indexing mechanism reaches a preselected line, generating a carriage return signal, actuating the carriage mechanism in response to said carriage return signal, generating an indexing signal in response to the actuation of the carriage return mechanism, automatically generating a plurality of successive indexing signals including the steps of sensing the automatic operation of the typewriter, generating a control signal in accordance therewith, inhibiting the indexing signals in response to the control signal, sensing the end of the previous indexing operation and enabling the next indexing signal when the end of the previous indexing operation is sensed, actuating the indexing mechanism in response to said indexing signals, and ceasing the actuation of the indexing mechanism in response to the indexing home signal.

135. The method of homing a carriage and indexing mechanism of an automatic typewriting system comprising the steps of sensing the line by line movement of the indexing mechanism and generating a home signal when the indexing mechanism reaches a preselected line, generating a carriage return signal, actuating the carriage mechanism in response to said carriage return signal, generating an indexing signal in response to the actuation of the carriage return mechanism, automatically generating a plurality of successive indexing signals includ-

154

ing the steps of sensing the automatic operation of the typewriter, generating a control signal in accordance therewith, inhibiting the indexing signals in response to the control signal, sensing the end of the previous indexing operation and enabling the next indexing signal when the end of the previous indexing operation is sensed, actuating the indexing mechanism in response to said next indexing signals, and inhibiting the actuation of the indexing mechanism in response to the indexing home signal.

136. The method of homing a carriage and indexing mechanism of an automatic typewriting system comprising the steps of sensing the line by line movement of the indexing mechanism and generating a home signal when the indexing mechanism reaches a preselected line, generating a carriage return signal, actuating the carriage mechanism in response to said carriage return signal, generating an indexing signal in response to the actuation of the carriage return mechanism, automatically generating a plurality of successive indexing signals including the steps of sensing the automatic operation of the typewriter, generating a control signal in accordance therewith, inhibiting the indexing signals in response to the control signal, sensing the end of the previous indexing operation and enabling the next indexing signal when the end of the previous indexing operation is sensed, actuating the indexing mechanism in response to said indexing signals, and inhibiting the generating of the indexing successive indexing signals in response to the indexing home signal by generating a second inhibit signal to cease the actuation of the indexing mechanism.

137. In an automatic writing system having a typewriter unit including carriage and indexing mechanisms, a format control system including coordinating means for generating a control signal for each line of movement of the indexing mechanism and circuit means generating a home signal in response to the movement to a preselected line, a program home circuit for prepositioning the indexing mechanism of the typewriter comprising, means for generating an initial signal, first circuit means connected to the carriage mechanism for initiating a carriage return function in response to said initial signal, and indexing circuit means connected to the indexing mechanism for producing successive indexing operations of the typewriter until the home signal is generated, and stop circuit means for discontinuing said indexing operation in response to the home signal.

138. In an automatic writing system having a typewriter unit including a carriage and indexing mechanism and a writing control system therefore, a format control system including coordinating means for generating a control signal for each line of movement of the indexing mechanism and circuit means generating a home signal in response to the movement to a preselected line, a program home circuit for prepositioning the indexing mechanism of the typewriter comprising, a home initiating circuit for generating a start signal, first circuit means connected to the carriage mechanism for initiating a carriage return function in response to said start signal, and indexing circuit means connected to the indexing mechanism for producing successive indexing operations of the typewriter until the home signal is generated, said indexing circuit means including bistable circuit means having a first and a second state in response to signals generated in the writing control system and signals generated in response to the indexing operation respectively.

139. In an automatic writing system having a typewriter unit including a carriage and indexing mechanism, a control system for said writing system, a format control system including coordinating means for generating a control signal for each line of movement of the indexing mechanism and circuit means generating a home signal in response to the movement to a preselected line, a program home circuit for prepositioning the carriage and indexing mechanism of the typewriter comprising, a home

155

initiating circuit for generating a start signal, first circuit means connected to the carriage mechanism for initiating a carriage return function in response to said start signal, and indexing circuit means connected to the indexing mechanism for producing successive indexing operations of the typewriter until the home signal is generated including gate circuit means having input circuit means generating an indexing signal in response to a preselected condition in the writing system control circuit, said gate circuit means having a plurality of input inhibit circuits, said inhibit circuits including stop circuit means generating an inhibit signal and impressing said inhibit signal on said gate means in response to the home signal and stopping the indexing operation.

140. In an automatic writing system having a typewriter unit including a platen, a format control system including coordinating means for generating a control signal for each writing space on a sheet of paper in the typewriter unit in response to the movement of the carriage and indexing mechanism of the typewriter and circuit means generating a preselected home signal, a program home circuit for prepositioning platen relative to the type imprinting mechanism of the typewriter comprising, a home initiating circuit for generating a start signal, first circuit means connected to the carriage mechanism for initiating a carriage return function in response to said start signal, and indexing circuit means connected to the indexing mechanism for producing successive indexing operations of the typewriter until the home signal is generated, and stop circuit means for discontinuing said indexing operation in response to the home signal.

141. In an automatic writing system having a typewriter unit including a platen space on a sheet of paper in the typewriter unit in response to the movement of the carriage and indexing mechanism of the typewriter and circuit means generating a preselected home signal, a program home circuit for prepositioning platen relative to the type imprinting mechanism of the typewriter comprising, a home initiating circuit for generating a start signal, first circuit means connected to the carriage mechanism for initiating a carriage return function in response to said start signal, and indexing circuit means connected to the indexing mechanism for producing successive indexing operations of the typewriter until the home signal is generated including gate circuit means having input circuit means generating an indexing signal in response to a preselected condition in the writing control system, said gate circuit means having a plurality of input inhibit circuits, said inhibit circuits including stop circuit means generating an inhibit signal and impressing said inhibit signal on said gate means in response to the home signal and stopping the indexing operation.

142. In an automatic writing system having a typewriter unit including a platen, a control system for said writing system, a format control system including coordinating means for generating a control signal for each writing space on a sheet of paper in the typewriter unit in response to the movement of the carriage and indexing mechanism of the typewriter and circuit means generating a preselected home signal, a program home circuit for prepositioning platen relative to the type imprinting mechanism of the typewriter comprising, a home initiating circuit for generating a start signal, first circuit means connected to the carriage mechanism for initiating a carriage return function in response to said start signal, and indexing circuit means connected to the indexing mechanism for producing successive indexing operations of the typewriter until the home signal is generated including gate circuit means having input circuit means generating an indexing signal in response to a preselected condition in the writing system control circuit including bistable circuit means having a first and second stable state, circuit means to selectively switch said bistable circuit means between said first and second states for sequentially generating indexing signals, and stop circuit

156

means generating a second inhibit signal and impressing said second inhibit signal on said gate means in response to the home signal and stopping the indexing operation.

143. In an automatic writing system having a typewriter that including a platen, a control system for said writing system, a format control system including coordinating means for generating a control signal for each writing space on a sheet of paper in the typewriter unit in response to the movement of the carriage and indexing mechanism of the typewriter and circuit means generating a preselected home signal, a program home circuit for prepositioning the platen relative to the type imprinting mechanism of the typewriter comprising, a home initiating circuit for generating a start signal, first circuit means connected to the carriage mechanism for initiating a carriage return function in response to said start signal, and indexing circuit means connected to the indexing mechanism for producing successive indexing operations of the typewriter until the home signal is generated including gate circuit means having input circuit means generating an indexing signal in response to a preselected condition in the writing system control circuit, said gate circuit means having a plurality of input inhibit circuits, a first of said inhibit circuit including bistable circuit means having a first and second state in response to signals generated in the control system and signals generated in response to the indexing operation, respectively, said first state acting to provide an inhibit signal to said gate circuit means and said second state acting to enable said gate circuit means, and circuit means to selectively switch said bistable circuit means between said first and second states for sequentially generating indexing signals.

144. In an automatic writing system having a typewriter unit including a platen and a writing control system therefore, and a format control system including coordinating means for generating a control signal for each writing space on a sheet of paper in the typewriter unit in response to the movement of the carriage and indexing mechanism of the typewriter and circuit means generating a preselected home signal, a program home circuit for prepositioning platen relative to the type imprinting mechanism of the typewriter comprising, a home initiating circuit for generating a start signal, first circuit means connected to the carriage mechanism for initiating a carriage return function in response to said start signal, and indexing circuit means connected to the indexing mechanism for producing successive indexing operations of the typewriter until the home signal is generated including bistable circuit means having a first and a second state in response to signals generated in the writing control system and signals generated in response to the indexing operation, respectively, said first state acting to provide an inhibit signal to said indexing circuit means and said second state acting to enable said indexing circuit means, and circuit means to selectively switch said bistable circuit means between said first and second states for sequentially generating indexing signals.

145. In an automatic writing system having a typewriter unit including a platen, a control system for said writing system, a format control system including coordinating means for generating a control signal for each writing space on a sheet of paper in the typewriter unit in response to the movement of the carriage and indexing mechanism of the typewriter and circuit means generating a preselected home signal, a program home circuit for prepositioning the platen relative to the type imprinting mechanism of the typewriter comprising a home initiating circuit for generating a start signal, first circuit means connected to the carriage mechanism for initiating a carriage return function in response to said start signal, and indexing circuit means connected to the indexing mechanism for producing successive indexing operations of the typewriter until the home signal is generated including gate circuit means having input circuit means generating an indexing signal in response to a preselected condition in the writing system control circuit including

75 ing an indexing signal in response to a preselected con-

157

dition in the writing system control circuit, said gate circuit means having a plurality of input inhibit circuits, a first of said inhibit circuit including bistable circuit means having a first and a second state in response to signals generated in the control system and signals generated in response to the indexing operation, respectively, said first state acting to provide an inhibit signal to said gate circuit means and said second state acting to enable said gate circuit means, circuit means to selectively switch said bistable circuit means between said first and second states for sequentially generating indexing signals and a second of said inhibit circuits including stop circuits means generating a second inhibit signal and impressing said second inhibit signal on said gate means in response to the home signal and stopping the indexing operation.

146. In an automatic writing system having a typewriter unit including a platen, a control system for said writing system, and a format control system including digital coordinating means for generating a control signal for each writing space on a sheet of paper in the typewriter unit in response to the movement of the carriage and indexing mechanism of the typewriter and circuit means generating a home signal in response to the movement of the platen to a preselected position, a program home circuit for prepositioning the platen to the home position relative to the type imprinting mechanism of the typewriter comprising, a home initiating circuit for generating a start signal, first circuit means including said home initiating circuit connected to the carriage mechanism for initiating a carriage return function in response to said start signal, and indexing circuit means connected to the indexing mechanism for producing successive indexing operations of the typewriter until the home signal is generated including gate circuit means, generating an indexing signal in response to a preselected condition in the writing system control circuit, said gate circuit means having a plurality of input inhibit circuits, a first of said inhibit circuit including control bistable circuit means having a first and a second state in response to signals generated in the control system and signals generated in response to the indexing operation, respectively, said first state acting to provide an inhibit signal to said gate circuit means and said second state acting to enable said gate circuit means, circuit means including the control circuit for selectively switching said control bistable circuit means between said first and second states for sequentially generating indexing signals and a second of said inhibit circuits including stop circuit means generating a second inhibit signal and impressing said second inhibit signal on said gate means in response to the home signal and stopping the indexing operation.

147. In an automatic writing system having a typewriter unit including a platen, a control system for said writing system, and a format control system including digital coordinating means for generating a control signal for each writing space on a sheet of paper in the typewriter unit in response to the movement of the carriage and indexing mechanism of the typewriter and circuit means generating a home signal in response to the movements of the platen to a preselected position, a program home circuit for prepositioning the platen to the home position relative to the type imprinting mechanism of the typewriter comprising, a home initiating circuit for generating a start signal including start bistable circuit means having first and second stable states, switching means and capacitor discharging circuit means for switching said bistable circuit means between said first and second stable states, first circuit means including said home initiating circuit connected to the carriage mechanism for initiating a carriage return function in response to said start signal, and indexing circuit means connected to the indexing mechanism for producing successive indexing operations of the typewriter until the home signal is generated including gate circuit means generating an indexing signal in response to a preselected

158

condition in the writing system control circuit, said gate circuit means having a plurality of input inhibit circuits, a first of said inhibit circuit including control bistable circuit means having a first and a second state in response to signals generated in the control system and signals generated in response to the indexing operation, respectively, said first state acting to provide an inhibit signal to said gate circuit means and said second state acting to enable said gate circuit means, circuit means including the control circuit selectively switching said control bistable circuit means between said first and second states for sequentially generating indexing signals and a second of said inhibit circuits including stop circuit means generating a second inhibit signal and impressing said second inhibit signal on said gate means in response to the home signal and stopping the indexing operation, said stop circuit means including stop bistable circuit means having first and second stable states, said home signal switching said stop bistable circuit means to the second stable state.

148. In a format control system for automatically controlling the operation of an automatic writing system having a reader unit sensing the movement of the carriage mechanism, the reader unit generating information signals in accordance with the position of the carriage mechanism, said reader unit having logic circuit means for storing coded information signals, a pulsing circuit for strobing the information signals generated in the reader unit comprising pulse producing means for generating a first pulse in accordance with a signal generated in the reader unit.

149. In a format control system for automatically controlling the operation of an automatic writing system having a reader unit sensing the movement of the carriage mechanism, the reader unit generating information signals in accordance with the position of the carriage mechanism, said reader unit having logic circuit means for the storing coded information signals, a pulsing circuit for strobing the information signals generated in the reader unit comprising first pulse producing means for generating a first pulse in accordance with a signal generated in the reader unit, logic circuit means producing a control signal in response to said first pulse, and second pulse producing means generating a second pulse in response to said control signal, said second pulse producing means being connected to the reader unit logic circuit means for strobing information signals contained therein.

150. In a format control system for automatically controlling the operation of an automatic writing system having a reader unit sensing the movement of the carriage mechanism, the reader unit generating information signals in accordance with the position of the carriage mechanism, said reader unit having logic circuit means for the storing coded information signal, a pulsing circuit for strobing the information signals generated in the reader unit comprising first pulse producing means for generating a first pulse in accordance with a signal generated in the reader unit, logic circuit means producing a control signal in response to said first pulse, second pulse producing means generating a second pulse in response to said control signal, said second pulse producing means being connected to the reader unit logic circuit means for strobing information signals contained therein, and inhibit circuit means connected to said logic circuit means for generating an inhibit pulse in response to certain operations of said writing system.

151. In a format control system for automatically controlling the operation of an automatic writing system having a reader unit sensing the movement of the carriage mechanism, the reader unit generating information signals in accordance with the position of the carriage mechanism, said reader unit having logic circuit means for the storing coded information signals, a pulsing circuit for strobing the information signals generated in the reader unit comprising first pulse producing means for generating a first pulse in accordance with a signal generated

159

in the reader unit, logic circuit means producing a control signal in response to said first pulse, second pulse producing means generating a second pulse in response to said control signal, said second pulse producing means being connected to the reader unit logic circuit means for strobing information signals contained therein, circuit means connecting said second pulse producing means to the other reader unit for strobing the coded information signals contained therein, and inhibit circuit means connected to said logic circuit means for generating an inhibit pulse in response to certain operations of said writing system, said inhibit circuit means including first circuit means responsive to the tabbing operation and second circuit means responsive to the carriage return operation.

152. In a format control system for automatically controlling the operation of an automatic writing system having a reader unit sensing the movement of the carriage mechanism, the reader unit generating information signals in accordance with the position of the carriage mechanism, said reader unit having logic circuit means for the storing coded information signals, a pulsing circuit for strobing the information signals generated in the reader unit comprising first pulse producing means for generating a first pulse in accordance with a signal generated in the reader unit, logic circuit means producing a control signal in response to said first pulse, second pulse producing means generating a second pulse in response to said control signal, said second pulse producing means being connected to the reader unit logic circuit means for strobing information signals contained therein, circuit means connecting said second pulse producing means to the other reader unit for strobing the coded information signals contained therein, and inhibit circuit means connected to said logic circuit means for generating an inhibit pulse in response to certain operations of said writing system, said inhibit circuit means including first circuit means responsive to the tabbing operation and second circuit means responsive to the carriage return operation, said second circuit means including bistable circuit means having a first and second state, said bistable circuit means being switched from the first to the second state by the operation of the carriage return function.

153. In a format control system for automatically controlling the operation of an automatic writing system having a reader unit sensing the movement of the carriage mechanism, the reader unit generating information signals in accordance with the position of the carriage mechanism, said reader unit having logic circuit means for the storing coded information signals, a pulsing circuit for strobing the information signals generated in the reader unit comprising a first single shot multivibrator for generating a first pulse in accordance with a signal generated in the reader unit, logic circuit means including gate circuit means producing a control signal in response to said first pulse, and a second single shot multivibrator generating a second pulse in response to said control signal, said second single shot multivibrator being connected to the reader unit logic circuit means for strobing information signal contained therein.

154. In a format control system for automatically controlling the operation of an automatic writing system having a reader unit sensing the movement of the carriage mechanism, the reader unit generating information signals in accordance with the position of the carriage mechanism, said reader units having logic circuit means for the storing coded information signals, a pulsing circuit for strobing the information signals generated in the reader unit comprising a first single shot multivibrator for generating a first pulse in accordance with a signal generated in the reader unit, logic circuit means including gate circuit means producing a control signal in response to said first pulse, and a second single shot multivibrator generating a second pulse in response to said control signal, said second single shot multivibrator being

160

connected to the reader unit logic circuit means for strobing information signals contained therein, circuit means connecting said second pulse producing means to the other reader unit for strobing the coded information signals contained therein, and inhibit circuit means connected to said logic circuit means for generating an inhibit pulse in response to certain operations of said writing system, said inhibit circuit means including first circuit means responsive to the tabbing operation and second circuit means responsive to the carriage return operation, said second circuit means including bistable circuit means having a first and second state, said bistable circuit means being switched from the first to the second state by the operation of the carriage return function.

155. In a format control system for automatically controlling the operation of an automatic writing system having a first reader unit sensing the movement of the indexing mechanism and a second reader unit sensing the movement of the carriage mechanism, the first and second reader units generating information signals in accordance with the respective positions of the indexing and carriage mechanism, said first and second reader units having logic circuit means for the storing coded information signals, a pulsing circuit for strobing the information signals generated in the first and second reader units comprising pulse producing means for generating a signal pulse in accordance with a signal generated in one of the reader units, said pulse producing means being connected to the one reader unit logic circuit means for strobing information signals contained therein, circuit means connecting said pulse producing means to the other reader unit for strobing the coded information signals contained therein, and circuit means connected to said pulse producing means sensing the movement of the indexing mechanism and generating a signal to actuate said pulse producing means, said pulse producing means generating a second pulse to strobe said other reader unit.

156. In a format control system for automatically controlling the operation of an automatic writing system having a first reader unit sensing the movement of the indexing mechanism and a second reader unit sensing the movement of the carriage mechanism, the first and second reader units generating information signals in accordance with the respective positions of the indexing and carriage mechanism, said first and second reader units having logic circuit means for the storing coded information signals, a pulsing circuit for strobing the information signals generated in the first and second reader units comprising first probe producing means for generating a signal pulse in accordance with a signal generated in one of the reader units, second pulse producing means generating a second pulse in response to said signal pulse, said second pulse producing means being connected to the one reader unit logic circuit means for strobing information signals contained therein, circuit means connecting said second pulse producing means to the other reader unit for strobing the coded information signals contained therein, and circuit means connected to said second pulse producing means sensing the movement of the indexing mechanism and generating a signal to actuate said second pulse producing means, said second pulse producing means generating a third pulse to strobe said other reader unit.

157. In a format control system for automatically controlling the operation of an automatic writing system having a first reader unit sensing the movement of the indexing mechanism and a second reader unit sensing the movement of the carriage mechanism, the first and second reader units generating information signals in accordance with the respective positions of the indexing and carriage mechanism, said first and second reader units having logic circuit means for the storing coded information signals, a pulsing circuit for strobing the information signals generated in the first and second reader units comprising first pulse producing means for generating a first pulse in accordance with a signal generated in one of the reader units,

logic circuit means producing a control signal in response to said first pulse, second pulse producing means generating a second pulse in response to said control signal, said second pulse producing means being connected to the one reader unit logic circuit means for strobing information signals contained therein, circuit means connecting said second pulse producing means to the other reader unit for strobing the coded information signals contained therein, and circuit means connected to said second pulse producing means sensing the movement of the indexing mechanism and generating a signal to actuate said second pulse producing means, said second pulse producing means generating a third pulse to strobe said other reader unit.

158. In a format control system for automatically controlling the operation of an automatic writing system having a first reader unit sensing the movement of the indexing mechanism and a second reader unit sensing the movement of the carriage mechanism, the first and second reader units generating information signals in accordance with the respective positions of the indexing and carriage mechanism, said first and second reader units having logic circuit means for the storing coded information signals, a pulsing circuit for strobing the information signals generated in the first and second reader units comprising a first single shot multivibrator for generating a first pulse in accordance with a signal generated in one of the reader units, logic circuit means including gate means for producing a control signal in response to said first pulse, a second single shot multivibrator generating a second pulse in response to said control signal, said second single shot multivibrator being connected to the one reader unit logic circuit means for strobing information signals contained therein, circuit means connecting said second single shot multivibrator to the other reader unit for strobing the coded information signals contained therein, circuit means connected to said second pulse producing means sensing the movement of the indexing mechanism and generating a signal to actuate said second pulse producing means, said second pulse producing means generating a third pulse to strobe said other reader unit, and inhibit circuit means connected to the input of said gate means for generating an inhibit signal and inhibiting said control signal in response to certain operations of the writing system.

159. In a format control system for automatically controlling the operation of an automatic writing system having a first reader unit sensing the movement of the indexing mechanism and a second reader unit sensing the movement of the carriage mechanism, the first and second reader units generating information signals in accordance with the respective positions of the indexing and carriage mechanism, said first and second reader units having logic circuit means for the storing coded information signals, a pulsing circuit for strobing the information signals generated in the first and second reader units comprising a first single shot multivibrator for generating a first pulse in accordance with a signal generated in one of the reader units, logic circuit means including gate means for producing a control signal in response to said first pulse, a second single shot multivibrator generating a second pulse in response to said control signal, said second single shot multivibrator being connected to the one reader unit logic circuit means for strobing information signals contained therein, circuit means connecting said second single shot multivibrator to the other reader unit for strobing the coded information signals contained therein, circuit means connected to said second pulse producing means sensing the movement of the indexing mechanism and generating a signal to actuate said second pulse producing means, said second pulse producing means generating a third pulse to strobe said other reader unit, and inhibit circuit means connected to the input of said gate means for generating an inhibit signal and inhibiting said control signal in response to certain operations of the writing system, said inhibit circuit means in-

cluding first circuit means responsive to the tabbing operation and second circuit means responsive to the carriage return operation.

160. In a format control system for automatically controlling the operation of an automatic writing system having a first reader unit sensing the movement of the indexing mechanism and a second reader unit sensing the movement of the carriage mechanism, the first and second reader units generating information signals in accordance with the respective positions of the indexing and carriage mechanism, said first and second reader units having logic circuit means for the storing coded information signals, a pulsing circuit for strobing the information signals generated in the first and second reader units comprising first pulse producing means for generating a first pulse in accordance with a signal generated in one of the reader units, logic circuit means producing a control signal in response to said first pulse, second pulse producing means generating a second pulse in response to said control signal, said second pulse producing means being connected to the one reader unit logic circuit means for strobing information signals contained therein, circuit means connecting said second pulse producing means to the other reader unit for strobing the coded information signals contained therein, and circuit means connected to said second pulse producing means sensing the movement of the indexing mechanism and generating a signal to actuate said second pulse producing means generating a third pulse to strobe said other reader unit, and inhibit circuit means connected to said logic circuit means for generating an inhibit pulse in response to certain operations of said writing system, said inhibit circuit means including first circuit means responsive to the tabbing operation and second circuit means responsive to the carriage return operation.

161. In a format control system for automatically controlling the operation of an automatic writing system having a first reader unit sensing the movement of the indexing mechanism and a second reader unit sensing the movement of the carriage mechanism, the first and second reader units generating information signals in accordance with the respective positions of the indexing and carriage mechanism, said first and second reader units having logic circuit means for the storing coded information signals, a pulsing circuit for strobing the information signals generated in the first and second reader units comprising first pulse producing means for generating a first pulse in accordance with a signal generated in one of the reader units, logic circuit means producing a control signal in response to said first pulse, second pulse producing means generating a second pulse in response to said control signal, said second pulse producing means being connected to the one reader unit logic circuit means for strobing information signals contained therein, circuit means connecting said second pulse producing means to the other reader unit for strobing the coded information signals contained therein, and circuit means connected to said second pulse producing means sensing the movement of the indexing mechanism and generating a signal to actuate said second pulse producing means generating a third pulse to strobe said other reader unit, and inhibit circuit means connected to said logic circuit means for generating an inhibit pulse in response to certain operations of said writing system, said inhibit circuit means including first circuit means responsive to the tabbing operation and second circuit means responsive to the carriage return operation, and a third single shot multivibrator for producing an output pulse in response to said control signal, said third single shot multivibrator being connected in feedback relation to said gate means for inhibiting said gate means for a predetermined period after said control signal is generated.

162. In an automatic writing system having a typewriter unit, a reader unit, a punch unit, first logic circuit means interconnecting the reader unit and the typewriter

163

unit, second logic circuit means interconnecting the typewriter unit and the punch unit and control circuit means for controlling the operation of the first and second logic circuit means, select circuit means for selectively deleting preselected groups of coded signals from portions of the first and second logic circuit means comprising first gate means having input terminals connected to the first logic circuit means for receiving a first group of coded signals to be deleted from the typewriter unit and the punch unit, second gate means having input terminals connected to the second logic circuit means for receiving a second group of coded signals to be deleted from the punch unit, third gate means having input terminals connected to the second logic circuit means for receiving a third group of coded signals to be deleted from the punch unit, each of said gate means having input circuit inhibit means for selectively inhibiting the operation of said gate means including switch means for selectively connecting the inputs of said gate means to a source of inhibiting potential, output bistable circuit means connected to said gate means and being switchable between first and second states in response to the outputs of said gates, said bistable means being connected to the control circuit to

164

selectively control the control circuit in accordance with the state of said bistable circuit means.
